UNITED STATES PATENT OFFICE

2,230,052

TELEPHONE SYSTEM

Thomas F. Crocker, Chicago, Ill., assignor to Associated Electric Laboratories, Inc., Chicago, Ill., a corporation of Delaware

Application February 17, 1939, Serial No. 256,901

80 Claims. (Cl. 179—27)

The present invention relates to telephone systems and, more particularly, to improved automatic switching apparatus of the character of that disclosed and claimed in the copending application of Thomas F. Crocker, Serial No. 5 142,558, filed May 14, 1937, now Patent No. 2,167,710, granted Aug. 1, 1939, which apparatus is connected and arranged to handle switchboard traffic.

10 A telephone system of this character conventionally comprises an automatic central office, a number of distant exchanges of any desired type, and interconnecting toll lines, the central office and each of the distant exchanges serving local 15 subscriber substations provided with subscriber lines. Local calls in the central office and in the distant exchanges of the automatic type are completed under the control of the subscribers at the subscriber substations; local calls in other 20 of the distant exchanges are completed in any suitable manner; and calls between the central office and the distant exchanges are completed by operators at a switchboard provided in the Central office. More particularly, the switch- 25 board which is provided in the central office comprises a number of operator positions, including groups of inward or toll operator positions, combined line and recording or C. L. R. operator positions, and delayed or point-to-point operator 30 positions.

In handling traffic at the switchboard, incoming calls from the distant exchanges are first 35 routed by way of the toll lines to the toll operator positions at the switchboard and then completed therefrom directly to the local subscriber substations in the central office, or transferred therefrom to the point-to-point operator positions to be completed later. Also, through calls 40 between the distant exchanges and including the central office are first routed by way of the toll lines to the toll operator positions at the switchboard and then extended therefrom by way of the toll lines to others of the distant exchanges. Outgoing calls originating at the subscriber substations in the central office which are to be extended to distant exchanges are first routed by way of C. L. R. trunks to the C. L. R. operator positions at the switchboard and then completed therefrom directly by way of the toll lines to 45 the distant exchanges, or transferred therefrom to the point-to-point operator positions to be completed later. In completing a call from a point-to-point operator position, the operator thereat first completes a connection to the called toll line or subscriber substation and then com-

pletes a connection to the calling toll line or subscriber substation.

The various toll and trunk calls are routed to and extended from the different operator positions by automatic switching apparatus including both local and toll switch trains, which apparatus is distributed for use and governed by suitable control means. Also, apparatus is provided at each operator position for answering calls 5 10 routed thereto, for supervising calls completed by way of the operator position, and for controlling the switching apparatus, thereby to extend and to initiate calls from the operator position. Furthermore, apparatus at each operator position is provided for performing the various 15 functions over the different toll, trunk and subscriber lines.

It is an object of the present invention to provide, in a telephone system of the character described and including a toll switch train associated with an operator position and a local switch train having access to a telephone line extending to a telephone station, an improved 20 trunk circuit disposed between the toll switch train and the local switch train which is so connected and arranged that a connection between 25 the operator position and the telephone station may be controlled and supervised in an improved manner.

It is another object of the invention to provide, 30 in a telephone system of the character described, a toll switch train associated with the operator position including an automatic switch which is connected and arranged in an improved manner.

Another object of the invention is to provide, 35 in a telephone system of the character described and including a number of operator positions and a group of trunk lines, an improved distributor arrangement for assigning the trunk lines 40 to be taken for use and for routing calls on the trunk lines taken for use to the operator positions 45 to be answered.

A further object of the invention is to provide, 50 in a telephone system of the character described and including a number of operator positions and two groups of trunk lines, two trunk distributors associated with the respective groups of trunk lines, which trunk distributors are so connected and arranged that calls on the trunk lines in the two groups are routed in a predetermined order to the operator positions 55 to be answered.

A further object of the invention is to provide, 60 in a telephone system of the character de-

5

45

55

scribed and including a number of operator positions and a distributor for routing incoming toll and trunk calls to the operator positions to be answered, operator controlled means at each of the operator positions for selectively converting the associated operator position from a universal toll and C. L. R. operator position to a toll operator position and to a point-to-point operator position.

10 It is a further object of the invention to provide, in a telephone system of the character described and comprising a central office provided with a number of operator positions and a community automatic exchange or C. A. X. network 15 including a number of exchanges and a number of trunks extending therebetween, an improved arrangement for completing calls between the exchanges in the C. A. X. network by way of the trunks and from the operator positions.

20 The invention is illustrated as being embodied in a telephone system comprising a central office of the automatic type, a community automatic exchange or C. A. X. network including a number of exchanges of the automatic type, and a 25 distant exchange of any suitable type. The central office serves a number of local subscriber substations and a number of local paystations; while the distant exchange and each of the exchanges in the C. A. X. network serve a number 30 of local subscriber substations. Local switch trains are provided in the central office and in each of the exchanges in the C. A. X. network, thereby to permit the local subscribers in the respective exchanges to complete local calls; while 35 local calls in the distant exchange are completed in any desired manner.

The C. A. X. network includes a tandem exchange and a number of other exchanges. Trunk lines are arranged between the other exchanges 40 and the tandem exchange in the C. A. X. network; C. A. X. trunks are arranged between the tandem exchange in the C. A. X. network and the central office; while toll lines are arranged between the distant exchange and the central office. Also, 45 C. L. R. trunks are arranged in the central office which are accessible to the local switch train therein.

A switchboard is arranged in the central office which comprises a number of operator positions. 50 Furthermore, a toll switch train is arranged in the central office which comprises a number of groups of finder-selector links individually associated with the operator positions at the switchboard and a group of delayed toll selector switches.

55 Each of the finder-selector links includes a finder switch and a toll selector switch. Each of the finder switches of the finder-selector links has access to each of the delayed toll selector switches, to each of the C. L. R. trunks, to each of the paystation lines in the central office, and to each 60 of the C. A. X. trunks; while each of the toll selector switches has access to the local switch train, to each of the paystation lines, to each of the toll lines, and to each of the C. A. X. trunks.

65 The local switch train comprises a number of finder-selector links each including a finder switch and a selector switch, and a number of connector switches accessible to the selector switches. Furthermore, a combined local and 70 toll connector switch is provided in the central office which is accessible to the selector switches of the local switch train and to the toll and delayed toll selector switches of the toll switch train. The local connector switches have access to the 75 local subscriber lines; while the combined local

and toll connector switches have access to the local subscriber lines and to the local paystation lines.

Also, apparatus is arranged at each of the operator positions for governing the operation of the finder-selector links associated therewith, thereby to answer, to extend, to initiate, and to supervise calls by way of the associated finder-selector links.

In accordance with one feature of the invention, a trunk circuit is interposed between the toll and delayed toll selector switches of the toll switch train and each of the local connector switches of the local switch train, which trunk circuit comprises a trunk line including first and 15 second branches. The first branch of the trunk line is accessible to the toll and delayed toll selector switches of the toll switch train; and the second branch of the trunk line is individually associated with a corresponding one of the local 20 connector switches of the local switch trains. Means under the control of the operators at the operator positions are provided for causing the toll and delayed toll selector switches of the toll switch train to seize the first branches of the 25 trunk lines and then to cause the local connector switches of the local switch train associated with the second branches of the trunk lines to seize the subscriber lines, thereby to extend calls from the operator positions to the subscriber substations 30 associated with the subscriber lines. A signal is provided at each of the operator positions, each of which is actuated under the control of any one of the trunk circuits when the call is extended to the subscriber substation and arrested under the 35 control of the trunk circuit when the call is answered at the subscriber substation. Furthermore, each of the trunk circuits comprises a normally completed metallic connection between the first and second branches of the trunk line and 40 a repeater, the trunk circuit being so connected and arranged that the metallic connection between the first and second branches of the trunk line is interrupted and an operative connection is completed therebetween by way of the repeater 45 when a call is extended thereover to a subscriber substation. Finally, each of the trunk circuits is so connected and arranged that the signal at any one of the operator positions may be actuated under the control of the subscriber at one of the 50 subscriber substations, thereby to give the subscriber at the subscriber substation switchhook supervision in order to signal the operator at the operator position.

Also, a trunk circuit of the general character of 55 that described above is arranged between the toll selector switches of the toll switch train and each of the combined local and toll connector switches, each of the last-mentioned trunk circuits being further connected and arranged to 60 control the operation of the associated combined local and toll connector switch to cause ringing current to be projected over a seized paystation line. Furthermore, each of the last-mentioned trunk circuits is further connected and arranged 65 to control by way of the associated combined local and toll connector switch the collection and refund of coin at a paystation associated with a paystation line seized by the associated combined local and toll connector switch.

In accordance with another feature of the invention, each of the toll and delayed toll selector switches in the toll switch train is of the type comprising a wiper set movable in both longitudinal and lateral directions, an associated con- 75

tact bank provided with a number of longitudinally spaced-apart rows of laterally spaced-apart contact sets, driving means for moving the wiper set with respect to the contact bank in a longitudinal direction and in a lateral direction, and a control network for governing the driving means. In each of the switches a first group of lines is terminated by contact sets disposed in a first row in the contact bank thereof; and a second group of lines is terminated by contact sets disposed in a second and a third row in the contact bank thereof. Furthermore, operator controlled means is provided at each of the operator positions for controlling the control network in each of the switches, and each of the control networks is so connected and arranged that the associated driving means is selectively governable to cause the associated wiper set selectively to engage a contact set in the associated contact bank terminating an idle line in the first group, a contact set in the associated contact bank terminating an idle line in the second group, and a contact set in the associated contact bank terminating any particular line in the second group. More particularly, each of the control networks is impulse responsive and responds to a given single digit to cause the associated switch to seize an idle line in the first group, to two given successive digits to cause the associated switch to seize an idle line in the second group, and to two other successive digits to cause the associated switch to seize a corresponding particular line in the second group.

In accordance with another feature of the invention, a C. L. R. trunk distributor is provided in the central office for causing the selector switches in the local switch train to seize in a predetermined order idle ones of the C. L. R. trunks. Further, a position distributor is provided for selecting in a predetermined order the groups of finder-selector links individually associated with the operator positions of the switchboard in which there are previously prepared links, operator controlled means being provided at each of the operator positions for preparing any one of the finder-selector links in the associated group of links to be selected by the position distributor. Furthermore, the C. L. R. trunk distributor is so connected and arranged that when a selector switch in the local switch train operates to seize an assigned C. L. R. trunk, it operates to cause another idle C. L. R. trunk to be assigned to be seized. Also, the C. L. R. trunk distributor operates to cause the position distributor to operate, thereby to cause a prepared one of the finder-selector links in a selected one of the groups to operate, whereupon the last-mentioned finder-selector link seizes the C. L. R. trunk which has been seized by the selector switch of the local switch train.

Means is provided in the tandem exchange for causing the C. A. X. trunks to be seized in a predetermined order, and a C. A. X. trunk distributor is provided in the central office, which is operative to cause the position distributor to operate, thereby to cause a prepared one of the finder-selector links in a selected one of the groups to operate and seize the C. A. X. trunk which has been seized in the tandem exchange. Furthermore, the C. A. X. trunk distributor is so connected and arranged that it causes the C. A. X. trunks to be seized in a predetermined order by the finder-selector links.

Furthermore, the C. L. R. trunk distributor is

normally operative in response to the presence of a call on any one of the C. L. R. trunks and remains operated until all of the calls on the C. L. R. trunks are answered at the switchboard; while the C. A. X. trunk distributor is normally 5 operative in response to the presence of a call on any one of the C. A. X. trunks and remains operated until all of the calls on the C. A. X. trunks are answered at the switchboard.

In accordance with a further feature of the invention, the C. L. R. trunk distributor and the C. A. X. trunk distributor are so interrelated that when one of these distributors is operated, the other of these distributors is prevented from being operated, thereby to cause all of the calls 10 of one type to be answered before any of the calls of the other type are answered, the type of calls first answered depending upon the type of call first extended to the switchboard. Moreover, the C. A. X. trunk distributor is so connected and 15 arranged that it is relatively slow to operate; whereas the C. L. R. trunk distributor is so connected and arranged that it is relatively fast to operate. Accordingly, in the event a C. A. X. trunk call and a C. L. R. trunk call are simultaneously initiated, the C. L. R. trunk call is first 20 answered at the switchboard.

In accordance with a further feature of the invention, the position distributor is normally 25 operative to cause a prepared one of the finder- 30 selector links in a selected one of the groups to operate and route both toll and trunk calls to the associated operator position to be answered. Operator controlled means is provided at each of the operator positions for restricting the 35 operation of the position distributor, whereby only toll calls are routed to the associated operator position to be answered. Additional operator controlled means is provided at each of the operator positions for preventing the position distributor 40 from selecting any one of the finder-selector links in the associated group when a delayed call is initiated at the associated operator position.

In accordance with another feature of the invention, switching means is provided in the tandem exchange which is controlled over calling ones of the lines in the C. A. X. network and which has access to the C. A. X. trunks. Also, first and second switching devices are associated with each of the C. A. X. trunks in the tandem 50 exchange and have access to each of the lines in the C. A. X. network. Apparatus is provided in the tandem exchange which is so connected and arranged that when the switching means seizes one of the C. A. X. trunks, the associated 55 first switching device is rendered operative by way of the C. A. X. trunk from any one of the operator positions at the switchboard in the central office. At this time, after the call on the C. A. X. trunk is answered at one of the operator 60 positions at the switchboard in the central office, the associated first switching device is controllable from the operator position in order to seize any one of the lines in the C. A. X. network, thereby to complete in the C. A. X. network an 65 operative reverting call connection between the calling and called lines. Further, it is noted that the operator at the operator position at the switchboard retains supervision of the completed connection and may release the first switching 70 device without releasing the connection between the calling line and the C. A. X. trunk. Accordingly, the operators at the operator positions at the switchboard may establish and supervise reverting call connections in the C. A. X. network. 75

Further, the apparatus in the tandem exchange is so connected and arranged that when one of the C. A. X. trunks is seized from one of the operator positions at the switchboard in the central office upon an outgoing call from the central office to the C. A. X. network, the associated second switching device is rendered operative by way of the C. A. X. trunk in order to establish a connection to any one of the lines in the C. A. X. network. Accordingly, the operators at the operator positions at the switchboard in the central office may extend outgoing calls to any one of the lines in the C. A. X. network. Further, it is noted that the apparatus in the tandem exchange is impulse responsive and operator controlled means is provided at each of the operator positions at the switchboard for controlling by way of a seized one of the C. A. X. trunks the first or second switching device operatively associated therewith, the switching device operatively associated with a seized C. A. X. trunk depending upon whether the C. A. X. trunk is seized upon a call from the C. A. X. network to the central office or upon a call from the central office to the C. A. X. network. Moreover, it is noted that the impulse responsive apparatus in the tandem exchange is controlled over any one of the C. A. X. trunks by way of a simplex link including the C. A. X. trunk. Also, a trunk circuit is associated with each of the C. A. X. trunks, which trunk circuit is so connected and arranged that both the calling and called lines in the C. A. X. network are given switchhook supervision in order to signal the operators at the operator positions at the switchboard.

Further features of the invention pertain to the particular arrangement of the circuit elements of the system, whereby the above-outlined and additional operating features are attained.

The novel features believed to be characteristic of the invention are set forth in the appended claims. The invention, both as to its organization and method of operation, together with further objects and advantages thereof, will best be understood by reference to the following specification taken in connection with the accompanying drawings, in which Figure 1 illustrates the general arrangement of a telephone system embodying the present invention; Figs. 2 to 15, inclusive, taken together, illustrate the details of a system having incorporated therein the features of the invention as briefly outlined above; and Fig. 16 illustrates the mode of combining Figs. 2 to 15, inclusive, to form a unified system.

55 DESCRIPTION OF THE APPARATUS INCORPORATED IN THE TELEPHONE SYSTEM

Referring now more particularly to Fig. 1 of the drawings, the telephone system there illustrated comprises a central office A, a distant exchange B, a distant community automatic exchange or C. A. X. network including a tandem exchange C and two exchanges D and E associated therewith. The central office A and each of the exchanges B, C, D and E serve a number of local stations, the local stations served by the central office A including both subscriber substations and paystations. More particularly, the central office A serves a number of local subscriber substations, including the subscriber substation indicated at T1 and associated with the subscriber line 962 extending to the central office, and a number of paystations, including the paystation indicated at T2 and associated with the paystation line 1501 extending to the central

office; while the tandem exchange C serves a number of subscriber substations, including the subscriber substation indicated at T3 and associated with the subscriber line 533 extending to the tandem exchange. The central office A and the distant exchange B are interconnected by a group of two-way toll lines of the ring-down type, including the toll line indicated at 340. The central office A and the tandem exchange C are interconnected by a group of two-way trunks, including the trunk indicated at 510. The tandem exchange C is interconnected with the exchanges D and E by two groups of trunks respectively including the trunks indicated at 532 and 531. Each of the toll lines extending between the central office A and the distant exchange B terminates in a ring-down toll line circuit individual thereto, the ring-down toll line circuit 310 being individual to the toll line 340. Each of the trunks extending between the central office A and the tandem exchange C terminates in a trunk circuit individual thereto, the trunk circuit 600 being individual to the trunk 510. Each of the subscriber and paystation lines extending to the various exchanges is provided with a line circuit individual thereto, the subscriber line 962 extending to the central office A being provided with a line circuit 961 individual thereto, and the paystation line 1501 extending to the central office being provided with a line circuit 1500 individual thereto. The central office A and each of the exchanges C, D and E are of the automatic type, while the distant exchange B may be of any desired type. Accordingly, the central office A and each of the exchanges C, D and E are provided with local switch trains which preferably comprise a plurality of groups of finder, selector and connector switches of the Strowger type arranged in the usual manner in order to set up the various connections between the local subscriber substations in the central office A and in the exchanges C, D and E. More particularly, the central office A is provided with a local switch train including the finder switch 471, the selector switch 472 and the connector switch 470. A number of reverting call switches, including the reverting call switch 473, are provided in the central office A and are accessible to the selector switches in the local switch train therein, thereby to permit local reverting calls to be completed from the local subscriber substations in the central office A. Also, the central office A is provided with a toll switch train, which preferably comprises a plurality of groups of finder, selector and connector switches of the Strowger type arranged in a manner more fully described subsequently, and which is utilized in setting up the various toll and trunk connections in a manner hereinafter described.

An automatic dial switchboard is arranged in the central office A and comprises a group of operator positions, each operator position having access to the toll switch train for the purpose of setting up the various toll and trunk connections.

More particularly, the toll switch train comprises a plurality of groups of finder-selector links individually associated with the operator positions at the toll board. The link finder switch 100 and the toll selector switch 800 comprise one of these links which is included in a group of links individually associated with the first operator position indicated at 1400. Also, a group of combined line and recording or C. L. R. trunks, including the C. L. R. trunk 450, is pro-

vided in the central office A, which trunks are accessible to the selector switches of the local switch train. More particularly, the C. L. R. trunk 450 is accessible to the selector switch 472 of the local switch train. Also, a C. L. R. trunk circuit is individually associated with each of the C. L. R. trunks, the C. L. R. trunk circuit 400 being individually associated with the C. L. R. trunk 450.

10 Each of the finder switches of the finder-selector links has access to each of the C. L. R. and C. A. X. trunks, to each of the toll lines extending between the central office A and the distant exchange B, to each of a group of delayed toll selectors, including the delay toll selector 480, included in the toll switch train, to each of the paystation lines in the central office A, and to the trunk circuit at the associated operator position. More specifically, the finder switch 700 of the 15 finder-selector link illustrated has access to the C. L. R. trunk 450 by way of the trunk line 460, to the C. A. X. trunk 510 by way of the trunk line 670, to the toll line 340 by way of the trunk line 321, to the delayed toll selector switch 480 by way of the trunk line 475, and to the paystation line 1501 by way of the trunk line 1514. Furthermore the finder switch 700 is accessible to the trunk circuit at the first operator position 1400 by way of the cable 1286. Also, each 20 of the toll and delayed toll selectors has access to each of the toll lines extending between the central office A and the distant exchange B, to each of the C. A. X. trunks, to a group of local connector switches included in the local switch train, and to a group of combination local and toll connector switches. More specifically, the delayed toll selector 480 and the toll selector 800 each has access to the toll line 340 by way of the trunk line 320, to the C. A. X. trunk 510 by way of the trunk line 680, to the local connector switch 960 by way of the trunk line 950, and to the combination local and toll connector switch 1090 by way of the trunk line 1080.

Also, it is noted that on outgoing trunk circuit 45 is interposed between each individual local connector switch and each individual combination local and toll connector switch and the delayed toll and toll selectors. More particularly, the outgoing trunk circuit 900 is individually interposed between the local connector switch 960 and the trunk line 950 extending to the delayed toll selector switch 480 and to the toll selector switch 800; and the outgoing trunk circuit 1000 is individually interposed between the combination local and toll connector switch 1090 and the trunk line 1080 extending to the delayed toll selector 480 and to the toll selector switch 800. The local connector switches have access to each subscriber line terminating at the central office 50 A; and the combination local and toll connector switches have access to each paystation line terminating at the central office A, thereby to permit toll and trunk connections to be extended to the local subscriber substations and paystations 55 in the central office.

70 Preferably, each of the operator positions, including the first operator position 1400 at the switchboard in the central office A, is of the universal type, thereby rendering it possible to render toll, C. L. R. and point-to-point service at each operator position. Also, each operator position is so connected and arranged that the service rendered thereby may be restricted to toll service. Common start and position distributor apparatus 75 330 is associated with the operator positions at

the switchboard, this apparatus being so connected and arranged that incoming calls to the switchboard are routed in a predetermined order to the operator positions to be answered.

Also, C. L. R. and C. A. X. trunk distributors 201 and 202, respectively, are provided which are so connected and arranged that C. L. R. and C. A. X. trunk calls are routed to the various operator positions to be answered in a predetermined order. More particularly, these distributors are so connected and arranged that all trunk calls of a particular type are routed to the various operator positions to be answered before any of the trunk calls of the other type are routed to the various operator positions to be answered, 15 the type of calls answered first being determined by the type of the first incoming call to arrive at the switchboard. This arrangement insures that all of the calls of a given type are answered before any of the calls of the other type are 20 answered.

Also individually associated with each operator position are one or more sender control circuits, the sender control circuit 300 being individually associated with the first operator position 1400. 25 Also, at each operator position there is provided a sending key set individual thereto which is associated with each of the sender control circuits associated with the operator position, the sending key set 303 being individually associated with the first operator position 1400 and with the sender control circuit 300. Finally, a group of digit register and control circuits is commonly associated with the switchboard. Each of the sender control circuits is provided with switching apparatus having access to each of the digit register and control circuits and is operative to select an idle digit register and control circuit when the sender control circuit is taken for use. Also, each of the sender control circuits is provided with 30 switching apparatus having access to the trunk circuit at the operator position individual thereto and to each of the finder-selector links individually associated with the particular operator position. More specifically, the sender control circuit 300 is individually associated with the first operator position 1400 by way of the trunk line 343 and is operatively associated with the sending key set 303 by way of the trunk line 342. 35 Also, the sender control circuit 300 has access to the digit register and control circuit 304 by way of the trunk line 341, to the trunk circuit at the first operator position 1400 by way of the cable 1367, and to the toll selector switch 800 of the finder-selector link illustrated by way of the 40 cable 786.

50 Preferably, the elements of the C. A. X. network, as best shown in Fig. 5, are connected and arranged in the manner described and claimed in U. S. Patent No. 1,759,869, Norman H. Saunders, granted May 27, 1930. Briefly, the C. A. X. network comprises a tandem exchange C and two exchanges D and E interconnected by two groups of trunks respectively including the trunks 532 and 534. Individually associated with each of the 55 trunks extending between the tandem exchange C and the exchanges D and E is a line switch, the line switch 521 being individually associated with the trunk 532 and the line switch 522 being individually associated with the trunk 531.

Also arranged in each of the exchanges C, D and E is a local switch train which is utilized in completing local calls in the particular exchange. More specifically, the local switch train included in the tandem exchange C comprises a 70 75

group of line switches individually associated with the subscriber lines terminating thereat, the line switch 520 being individually associated with the subscriber line 533, a plurality of selector switches, including the selector switch 518, accessible to each of the line switches, and a plurality of connector switches, including the connector switch 519, accessible to each of the selector switches and having access to the subscriber lines. Preferably, each of the line switches is of the well-known rotary type, while each of the selector and connector switches is of the well-known Strowger type.

Also included in the tandem exchange C is a group of trunk lines, each trunk line including a number of branches, the trunk line illustrated including the branches 501, 502, 503 and 504. Each of the trunk lines included in the tandem exchange C is accessible to each of the line switches in the groups of line switches respectively including the line switches 521 and 522 and to each of the selector switches in the group including the selector switch 518. Also, a control circuit and repeater is individually associated with each trunk line in the tandem exchange, the control circuit and repeater 500 being individually associated with the trunk line illustrated.

Preferably each of the trunk lines is connected and arranged in the manner of the trunk line indicated, the branches 501 and 502 being individually provided with the selector switches 516 and 517, respectively, and the branch 504 being associated with the C. A. X. trunk line 510 extending to the central office A. More particularly, the control circuit and repeater 500 associated with the trunk line illustrated is so connected and arranged that ordinary trunk calls may be extended from the central office A over the C. A. X. trunk line 510 and the control circuit and repeater 500 by way of the selector switch 516 to the local switch train in the tandem exchange C or to the local switch trains in either of the exchanges D or E. Also, the control circuit and repeater 500 is so connected and arranged that a dual or reverting call may be set up from the central office A over the C. A. X. trunk line 510 by way of the control circuit and repeater 500 and the selector switch 517 to the local switch train in the tandem exchange C or to the local switch train in either the exchanges D or E, while the branch 503 of the trunk line illustrated is seized by one of the selector or line switches having access thereto. Also, it is noted that the control circuit and repeater 500 individually associated with the C. A. X. trunk line 510 is controlled over the branch 503 of the trunk illustrated and over the control conductor C515, the last mentioned control conductor being connected to the neutral point between two impedance elements 513 and 514 extending between the line conductors C511 and C512 of the C. A. X. trunk line 510, thereby to provide a simplex link. Finally, it is noted that the line conductors C505 and C506 of the branch 504 of the trunk line illustrated are capacitively coupled to the line conductors C511 and C512, respectively, of the C. A. X. trunk line 510 by the condensers 507 and 508, respectively.

Preferably, each of the trunk circuits terminating the C. A. X. trunks in the central office A is identical to the trunk circuit 600 terminating the C. A. X. trunk 510. As best shown in Fig. 6, the trunk circuit 600 comprises a repeater 633 operatively associated with the C. A. X. trunk 510 and with the trunk lines 670 and 680 ex-

tending to the finder-connector links disposed at the switchboard. Also, the trunk circuit 600 comprises a relay network including a start relay R640, a dial-out relay R620, a marking relay R650 and a number of control relays R610, R630 and R660 connected in a manner more fully described subsequently.

Preferably, each of the C. L. R. trunk circuits terminating the C. L. R. trunks in the central office A is identical to the C. L. R. trunk circuit 400 which comprises, as best shown in Fig. 4, a repeater 410 operatively associated with the C. L. R. trunk 450 and with the trunk line 460 extending to the finder switches of the finder-selector links at the switchboard. Also, the trunk circuit 400 comprises a relay network including a number of control relays R420, R430 and R440 connected and arranged in a manner more fully described subsequently.

Preferably, each of the trunk circuits included in each of the trunk lines extending to each of the local connector switches is identical to the trunk circuit 900 which comprises, as best shown in Fig. 9, a repeater 910 operatively associated with the trunk line 955 extending to the local connector switch 960 and with the trunk line 950 extending to the toll selector and delayed toll selector switches. Also, the trunk circuit 900 comprises a relay network including a number of control relays R920, R930 and R940 connected and arranged in a manner more fully described subsequently. Preferably, each of the trunk circuits included in each of the trunk lines extending to the combined local and toll connector switches is identical to the trunk circuit 1000 which comprises, as best shown in Fig. 10, a repeater 1010 operatively associated with the trunk line 1084 extending to the combined local and toll connector switch 1090 and with the trunk line 1080 extending to the toll selector and delayed toll selector switches. Also, the trunk circuit 1000 comprises a relay network including a number of control relays R1020, R1030, R1040, R1050, R1060 and R1070 connected and arranged in a manner more fully described subsequently.

Preferably, each of the line circuits terminating the toll lines in the central office A is identical to the line circuit 310 which is, as indicated in Fig. 3, a ring-down toll line circuit of any suitable connection and arrangement. The specific connection and arrangement of the ring-down toll line circuit 310 is not disclosed as the details thereof form no part of the present arrangement.

Preferably each of the line circuits terminating the subscriber lines extending to the central office A from local subscriber substations is identical to the line circuit 961 which is, as indicated in Fig. 9, a substation line circuit of any suitable connection and arrangement. The specific connection and arrangement of the substation line circuit is not disclosed as the details thereof form no part of the present invention.

Preferably, each of the line circuits terminating the paystation lines extending to the central office A from local paystations is identical to the paystation line circuit 1500 which comprises, as best shown in Fig. 15, a number of control relays R1520, R1530 and R1540 connected and arranged in a manner more fully described subsequently.

The C. L. R. trunk distributor 201 and the C. A. X. trunk distributor 202 are so connected and arranged that C. L. R. trunk calls and

- C. A. X. trunk calls incoming to the central office A are assigned to be answered at the switchboard in a predetermined order, as previously noted. As best shown in Fig. 2, the C. L. R. 5 trunk distributor 201 comprises a relay network including a start relay R230 and a number of control relays R210, R215, R220 and R225 connected and arranged in a manner more fully described subsequently. As best shown in Fig. 10 2, the C. A. X. trunk distributor 202 comprises a relay network including a start relay R260 and a number of control relays R240, R245, R250 and R255 connected and arranged in a manner more fully described subsequently.
- 15 Preferably, each of the finder, selector and connector switches included in the local switch train in the central office A is identical to the finder, selector and connector switches indicated in Fig. 4 at 471, 472 and 470, respectively. Also, 20 the local connector switches and combined local and toll connector switches included in the toll switch train are identical to the local connector switch and combined local and toll connector switch indicated in Figs. 9 and 10, respectively, 25 at 960 and 1090, respectively. Moreover, each of these switches is of the well-known Strowger type and is connected and arranged in the usual manner. The specific connections and arrangements of these switches are not described as the 30 details thereof form no part of the present invention.
- 35 Preferably, each of the operator positions at the automatic dial switchboard is identical to the operator position 1400 which comprises a set of position keys 1400A, position telephone equipment 1100A and a relay group 1200A. As best shown in Fig. 14, the set of position keys 1400A arranged at the first operator position 1400 comprises a coin return key K1, a coin collect key K2, an error key K3, a dial rear key K4, a ring key K5, a cut-off key K6, a release and start key K7, a release key K8, a transfer key K9, a toll answer key K10 and a dual release key K11. Also associated with the first operator position are a group of toll answer 40 lamps including the toll answer lamp L1462 and a group of trunk answer lamps including the trunk answer lamp L1463. The connections and arrangements of the keys and lamps mentioned are described in detail hereinafter. The 45 telephone equipment 1100A at the first operator position comprises, as best shown in Fig. 11, a receiver 1148, a transmitter 1147, a talking repeater 1106 and a monitoring repeater 1102, the last-mentioned repeaters being operatively associated with the telephone instrument at the first operator position and with the trunk circuit thereat in a manner more fully described 50 hereinafter.
- 50 The relay group 1200A arranged at the first operator position 1400 comprises, as best shown in Figs. 11, 12 and 13, a number of relays including a transmitter supply relay R1100, a monitor relay R1110, a talking relay R1130, a transfer relay R1200, a front split relay R1210, a rear split relay R1220, a supervisory relay R1230, a rear coin control relay R1250, an answer pilot relay R1260, an error relay R1270, a distributor start relay R1310, a call pilot relay R1320, a cut-in relay R1330, a call relay R1340 and a number of control relays R1120, R1140, R1150, R1160, R1240, R1300 and R1350. Certain of the relays mentioned are connected and arranged for the purpose of controlling the association of the 55 telephone instrument at the first operator position with the trunk circuit thereat; other of the relays mentioned are so connected and arranged that they control the transmission of tone to the receiver of the telephone instrument at the first operator position when an incoming call is routed to the first operator position. Finally, the remainder of the relays mentioned are so connected and arranged that various types of toll and trunk calls may be initiated, answered, released and supervised from the first 60 operator position in a manner more fully described subsequently.
- 65 As previously noted, a group of finder-selector links is individually associated with each operator position, the finder-selector link comprising the finder switch 700, shown in Fig. 7, and the selector switch 800, shown in Fig. 8, being included in the group of finder-selector links individually associated with the first operator position 1400. Preferably, each of the 70 finder-selector links is identical to the finder-selector link illustrated, the finder switch of each of the finder-selector links being operatively associated with the cable 1286 extending to the trunk circuit at the first operator position 1400.
- 75 The finder switch 700 comprises a switching mechanism 701 of the Strowger type including a wiper set provided with a number of wipers 702 to 708, inclusive, and capable of both linear and rotary movements. Further, the mechanism 701 comprises a circumferentially disposed main contact bank including ten vertical levels of contact sets arranged in circumferentially spaced-apart relationship. Also, the mechanism 701 includes a vertical control contact bank 709 associated with the vertical control wiper 708 of the wiper set. The mechanism 701 is provided with a vertical magnet M133 for moving the wiper set thereof in the vertical direction, a rotary magnet C134 for moving the wiper set thereof in the rotary direction, and a release magnet M135 for releasing the wiper set thereof and for causing the wiper set to be returned to its normal position. Finally, the mechanism 701 has a number of sets of switch springs S183, S184 and S185 operatively associated therewith which are controlled in accordance with the movements of the wiper set thereof in a manner more fully described subsequently.
- 80 Also, the finder switch 700 comprises a number of relays including an electropolarized relay R710, a switch-over relay R720, a step relay R730, a start relay R740, a connect relay R750 and a cut-through relay R760 connected and arranged in a manner more fully described subsequently. Moreover, the finder switch 700 has individually associated therewith a link listening or talk key 780 and a monitoring key 770 which are operative to associate the finder switch 700 with the cable 1286 extending to the trunk circuit at the first operator position. Finally, a number of supervisory lamps L776, L767 and L768 are associated with the finder switch 700 for supervisory purposes.
- 85 The toll selector switch 800 comprises a switching mechanism 801 of the Strowger type including a wiper set provided with a number of wipers 802 to 807, inclusive, and capable of both linear and rotary movements. Further, the mechanism 801 comprises a circumferentially disposed main contact bank including ten vertical levels of contact sets arranged in circumferentially spaced-apart relationship. Also, the mechanism 801 includes a vertical control contact bank 809

comprising two portions 821 and 822 associated with the vertical control wiper 807 of the wiper set. Moreover, the mechanism 801 is provided with a vertical magnet M801 for moving the wiper set thereof in the vertical direction, a rotary magnet M802 for moving the wiper set thereof in the rotary direction, and a release magnet M805 for releasing the wiper set thereof and for causing the wiper set to be returned to its normal position. Finally, the mechanism 801 has a number of sets of switch springs S898, S899, S806, S895 and S810 operatively associated therewith which are controlled in accordance with the movements of the wiper set thereof in a manner more fully described subsequently. Also, the toll selector switch 800 comprises a number of relays, including an electropolarized relay R810, a line relay R820, a hold relay R830, and a number of control relays R840, R850, R860, R870, R880, R885 and R890, connected and arranged in a manner more fully described subsequently.

Preferably, each of the delayed toll selector switches, including the delayed toll selector switch 480 illustrated in Fig. 4, is identical to each of the toll selector switches included in the finder-selector links. For example, the delayed toll selector switch 480 is identical to the toll selector switch 800 forming a part of the finder-selector link illustrated and described above.

As previously noted, one or more sender control circuits are individually associated with each operator position, the sender control circuit 300 illustrated in Fig. 3 being individually associated with the first operator position 1400. Preferably, each of the sender control circuits is identical to the sender control circuit 300 which is connected and arranged in any suitable manner. However, it is preferable that the sender control circuit 300 be connected and arranged as disclosed in the previously mentioned copending application of Thomas F. Crocker. The details of the connection and arrangement of the sender control circuit 300 are not disclosed herein as they do not form a part of the present invention. However, it is noted that the sender control circuit 300 comprises two rotary switches 301 and 302, the rotary switch 301 having access to each of the digit register and control circuits commonly associated with the operator positions at the toll board. The rotary switch 302 has access to a number of cables individually extending to the finder-selector links individually associated with the first operator position 1400 and has access to the trunk circuit disposed at the first operator position 1400. More specifically, the rotary switch 302 has access to the cable 786 extending to the illustrated finder-selector link associated with the first operator position, to the cables corresponding to the cable 786 and individually extending to the other finder-selector links associated with the first operator position, and to the cable 1367 which is connected to the trunk circuit disposed at the first operator position.

A group of digit register and control circuits, including the digit register and control circuit 304, is commonly associated with the operator positions at the switchboard. Preferably, each of the digit register and control circuits is identical to the digit register and control circuit 304 which is arranged in any suitable manner. However, it is preferable that the digit register and control circuit 304 be connected and arranged as disclosed in the above-mentioned copending

application of Thomas F. Crocker. The details of the connection and arrangement of the digit register and control circuit 304 are not disclosed herein as they do not form a part of the present invention.

A sending key set is arranged at each operator position as previously noted, the sending key set 303, illustrated in Fig. 3, being arranged at the first operator position 1400. The sending key set 303 may be of any suitable construction and comprises ten digit keys and a send disconnect key of the usual construction and arrangement. The details of the sending key set 303 have not been illustrated as they form no part of the present invention.

The common start and position distributor apparatus 330, illustrated in Fig. 3, is operatively associated with each of the operator positions at the switchboard, each of the finder-selector links associated with the operator positions at the switchboard, each of the ring-down toll line circuits, each of the paystation line circuits, the C. L. R. trunk distributor 201, and the C. A. X. trunk distributor 202. The details of the connection and arrangement of the common start and position distributor apparatus 330 are not disclosed as they form no part of the present invention. However, it is noted that the common start and position distributor apparatus 330 is so connected and arranged that incoming toll and trunk calls are distributed thereby to the various operator positions at the toll board to be answered in a predetermined order, as will appear more fully hereinafter.

A better understanding of the connection and arrangement of the apparatus incorporated in the telephone system will be facilitated from a consideration of the detailed operation of the various pieces of apparatus incident to the handling of the various toll and trunk calls at the switchboard, as will appear hereinafter.

Preselecting a finder-selector link

When an operator at one of the operator positions at the switchboard is not engaged and wishes to answer a call incoming to the switchboard, she first selects an idle finder-selector link individually associated with her position and operates the link listening or talk key thereof away from its normal position. For example, assuming that the operator at the first operator position 1400 is not engaged and wishes to answer a call incoming to the switchboard, she first selects an idle finder-selector link individually associated with her position. Assuming that the finder-selector link illustrated is idle, the operator at the first operator position operates the talk key 780 thereof away from its normal position, this finder-selector link being indicated as idle by the unlighted condition of the busy lamp L168.

At this time the plugs terminating the conductors of the transmitter 1147 and the receiver 1148 at the first operator position occupy inserted positions in the associated jacks. Accordingly, the transmitter 1147 and the receiver 1148 are operatively associated with the trunk circuit at the first operator position. More particularly, operating current is supplied to the transmitter 1147 by way of a circuit including the windings of the transmitter supply relay R1100, the last-mentioned circuit extending from ground by way of the lower winding of R1100, the jack ring 1126, the plug ring 1124, the transmitter 1147, the plug ring 1155, the jack ring 1157, 75

the winding 1108 of the talking repeater 1106, and the upper winding of R1100 to battery.

It is noted that the relay R1100 is energized over the above-traced circuit and occupies its 5 operated position. Moreover, it is noted that a condenser 1129 is connected across the terminals of the upper and lower windings of the relay R1100, thereby to provide a voice frequency current path for operatively associating the transmitter 1147 with the winding 1108 of the repeater 1106, which path excludes the windings of the relay R1100. Also, at this time, the receiver 1148 is operatively associated with the winding 1107 of the repeater 1106 by way of a circuit extending 10 from the receiver 1148 over the plug tip 1123, the jack tip 1125, the conductor C1172, RA1118, RC1118, the conductor C1171, the condenser 1128, the right-hand portion of the winding 1107 of the repeater 1106, the condenser 1127, the conductor C1174, RC1116, RA1115, the conductor C1173, the jack tip 1158 and the plug tip 1156 15 to the receiver 1148.

The operated relay R1100 prepares, at RA1101, a circuit for energizing the lower winding of the 20 connect relay in any one of the finder switches of the finder-selector links associated with the first operator position 1400 when the talk key of the corresponding finder switch is operated away from its normal position, and completes at RA1101 an obvious path for applying ground potential to the conductor C1188, thereby to condition the sender control circuit 300 to be operative in a manner more fully described hereinafter. Accordingly when the talk key 780 of the 25 finder switch 700 is operated away from its normal position, as previously noted, a circuit is completed for energizing the lower winding of the connect relay R750. The last-mentioned circuit extends from ground at RA1101 by way of C1188, RA1137, RC1139, C1186, RC1200, RA1209, the conductor C1285 disposed in the cable 1286, the contact 782 of the talk key 780, and the lower winding of R750 to battery. When energized over the above-traced circuit, the connect relay 30 R750 operates to complete, at RA750, a holding circuit for energizing the upper winding thereof in series with the winding of the talk relay R1130, this circuit extending from ground by way of the winding of R1130, C1183, RC1207, RA1207, the 35 conductor C1283 disposed in the cable 1286, the contact 781 of the talk key 780, RA750 and the upper winding of R750 to battery. Shortly after the above-traced circuit is completed, the talk relay R1130, being of the slow-to-operate type, 40 operates to interrupt, at RA1137 and RC1139, a point in the previously traced path for applying ground potential to the conductor C1285 disposed in the cable 1286, thereby to interrupt the previously traced circuit for energizing the lower winding of the connect relay R750 and to prevent the connect relay of any one of the other 45 finder switches from being operated inadvertently. Also, upon operating, the talk relay R1130 operates to interrupt, at RA1131, a point in a path for applying ground potential to the control conductor C1166 of the trunk 1165 extending to the chief operator position. When ground potential is removed from the control conductor C1166, a lamp 50 at the chief operator position is extinguished, thereby to indicate to the chief operator that the operator at the first operator position is busy. 55

Also, upon operating, the talk relay R1130 interrupts, at RA1136, a point in a circuit, traced hereinafter, for energizing the monitoring relay 60 R1110, thereby to prevent operation of the last-

mentioned relay at this time. Also the talk relay R1130 interrupts, at RA1132 and RC1132 and at RA1134 and RC1134, points in the path for connecting the winding 1103 of the monitoring repeater 1102 across the trunk conductors C1180 5 and C1181 at the first operator position, and completes, at RA1132 and RC1133 and at RA1134 and RC1135, a path for operatively connecting the winding 1101 of the talking repeater 1106 across the line conductors C1180 and C1181 of 10 the trunk circuit at the first operator position. At this time the telephone instrument at the first operator position is operatively associated with the trunk circuit thereat, the winding 1107 of the talking repeater 1106 being connected 15 across the line conductors of the trunk circuit at the first operator position as previously noted. More specifically, one terminal of the winding 1107 is connected by way of the conductor C1170, RC1133 and RA1132 to the line conductor C1180; 20 and the other terminal of the winding 1107 is connected by way of the condenser 1128, C1171, RC1135 and RA1134 to the line conductor C1181. Accordingly, at this time, the telephone instrument at the first operator position is operatively 25 associated with the trunk circuit thereat, thereby to permit the operator at this position to communicate in either direction by way of the trunk circuit.

Finally, the talk relay R1130 completes, at 30 RA1131 and RC1138, a circuit for energizing the winding of the distributor start relay R1310, this circuit extending from ground at RA1101 by way of C1188, RA1137, RC1138, C1187, RA1273, RA1266, C1385, the winding of R1310, RA1321, 35 C1453 and the contact 1447 of the toll answer key K10 to battery. Shortly after the distributor start relay R1310 is energized over the above-traced circuit, the latter relay being of the slow-to-operate type, it operates to interrupt, at 40 RA1312 and RC1313, a point in the path for applying ground potential to the guard conductor C1371 and completes, at RA1312 and RC1314, a point in a path for applying ground potential to the start conductor C1370. Further, the distributor start relay R1310 prepares, at RA1311, a point in a circuit, traced hereinafter, for energizing the start relay R740 of the finder switch 700 and prepares, at RA1315, a point in a circuit, traced hereinafter, for energizing the relay R1140 45 included in the relay network for impressing tone upon the line conductors of the trunk circuit at the first operator position. It is noted that the removal of ground potential from the guard conductor C1371 and the application of ground potential to the start conductor C1370 control the operation of the common start and position distributor apparatus 330 by way of the cable 1374 extending to the common start and position distributor apparatus 330. More specifically, the removal of ground potential from the guard conductor C1371 marks the first operator position 50 1400 as a position to which a call incoming to the switchboard is to be extended, and the application of ground potential to the start conductor C1370 causes the common start and position distributor apparatus 330 to operate and select one of the operator positions to have an incoming call extended thereto if it has not previously selected 55 one of the operator positions. It is pointed out that the operator positions are preselected in a predetermined order by the common start and position distributor apparatus 330 to have an incoming call to the switchboard routed thereto to 60 70 75

be answered. Accordingly, the next time the common start and position distributor apparatus 330 tests the first operator position 1400, this position will be selected to have the next incoming 5 call to the toll board routed thereto. Accordingly, it will be assumed at this time that the first operator position has been selected by the common start and position distributor apparatus 330 to have the next incoming call to the switchboard routed thereto to be answered.

Also, upon operating, the connect relay R150 in the finder switch 700 prepares, at RA151, a circuit, traced hereinafter, for energizing the answer pilot relay R1260 and prepares, at RA152 and RA153 and at RA155 and RA156, points in a circuit, traced hereinafter, for connecting the trunk circuit at the first operator position 1400 to the wipers 702 and 703 of the wiper set included in the mechanism 701 of the finder switch 700. 15 Further, the connect relay R750 interrupts at RA152' and RC754' a point in an obvious path for applying ground potential to the control conductor C792 of the cable 786, thereby to mark the cable 786 as having a calling condition thereon. 20 At this time the apparatus at the first operator position and the apparatus in the finder switch 700 of the finder-selector link illustrated are in condition to receive the next incoming call to the switchboard, and the next incoming call to the switchboard will be routed to the first operator position 1400 in a manner more fully described 25 subsequently.

Extension of a call from a local subscriber substation in the central office A to the switchboard

In order to establish a connection between a local subscriber substation in the central office A and the switchboard, the subscriber at the local subscriber substation first removes the receiver of the telephone instrument thereat, thereby to obtain a connection to the local switch train in the central office. Assuming that the subscriber at the local subscriber substation T1 desires a connection to the switchboard in the central office A, he removes the receiver of the telephone instrument thereat from its hook, thereby to cause the line circuit 961 associated with the subscriber line 962 extending to the subscriber substation T1 to operate and mark the subscriber line 962 as a calling line, whereupon the finder switch 471 of the local switch train operates and seizes the calling subscriber line 962 in the usual manner. When the finder switch 471 operates to seize the calling subscriber line 962, it further operates to cause the selector switch 472 associated therewith to be conditioned to be responsive to impulses and to return dial tone current over the calling subscriber line 962, thereby to indicate to the subscriber at the calling substation T1 that he may operate the dial mechanism thereat in order to extend the connection further. The subscriber at the calling substation T1 then dials a single digit, preferably the digit 0, thereby to cause the selector switch 472 to operate automatically and search for an idle C. L. R. trunk extending to the switchboard and assigned by the C. L. R. trunk distributor 201 for use. Assuming that the C. L. R. trunk 450 is the first 65 available C. L. R. trunk extending to the switchboard and is assigned by the C. L. R. trunk distributor 201 for use, the selector switch 472 operates and seizes this C. L. R. trunk. The manner in which the C. L. R. trunk distributor 201 70 operates to assign the C. L. R. trunks to be seized

will be described hereinafter. However, it is noted that the C. L. R. trunk 450 is marked to be seized by the presence of battery potential upon the control conductor C451 thereof, this potential being applied to the control conductor C451 by way of a path extending from battery at the upper winding of the relay R215 in the C. L. R. trunk distributor 201 and extending therefrom by way of the upper winding of R215, RA221 and C265 to the control conductor C451. 10

When the selector switch 472 seizes the C. L. R. trunk 450, a loop circuit is completed in the selector switch 472 including the upper and lower windings of the relay R440 in the C. L. R. trunk circuit 400 and extending to the calling subscriber substation T1. The last-mentioned loop circuit extends from ground at the lower winding of R440 by way of the lower winding of R440 and the winding 413 of the repeater 410 to the line conductor C453 of the C. L. R. trunk 450 and from battery at the upper winding of R440 by way of the upper winding of R440 and the winding 411 of the repeater 410 to the line conductor C452 of the C. L. R. trunk 450, the line conductors C452 and C453 of the C. L. R. trunk 450 25 being connected by way of the selector switch 472, the finder switch 471 and the subscriber line 962 to the calling subscriber substation T1. When the above-mentioned loop circuit is completed, the relay R440 is energized and operates to complete, at RA444, a circuit for returning a signalling tone over the calling subscriber line, and completes, at RA441 and RC443, an obvious circuit for energizing the relay R430, thereby to cause the latter relay to operate shortly thereafter, the latter relay being of the slow-to-operate type. The circuit for returning the signalling tone over the calling subscriber line extends from ground in the selector switch 472 by way of the calling subscriber line, the line conductor C453 40 of the C. L. R. trunk 450, RA444, the condenser 417, RA425 and L418 to the tone conductor C418, the last-mentioned conductor being connected to the ungrounded terminal of a grounded winding of a tone current transformer. When the circuit 45 traced above is completed, the signalling tone current applied to the C. L. R. trunk 450 is returned over the local switch train including the selector switch 472 and the finder switch 471 to the subscriber line 962, thereby to produce a 50 tone in the receiver of the telephone instrument at the calling subscriber substation T1 in order to indicate to the calling subscriber thereat that the initiated call is receiving attention. Upon operating, the relay R430 completes, at RA431, an obvious path for applying battery potential at the winding of the relay 420 to the control conductor C462 of the trunk line 460 extending to the finder switch 700, completes, at RA432, an obvious 55 circuit for applying ground potential at RA432 to the control conductor C451 of the C. L. R. trunk 450, and completes, at RA433, a path, traced hereinafter, for applying ground potential to the start conductor C268 extending to 60 the C. L. R. trunk distributor 201. 65

The path for applying ground potential to the start conductor C268 extends from ground at RA422 by way of RC424 and RA433 to the start conductor C268. This application of ground potential to the start conductor C268 completes a path for energizing the winding of the start relay R230 in the C. L. R. trunk distributor 201, provided the start relay R260 in the C. A. X. trunk distributor 202 is not operated at this time, 75

as will be explained more fully hereinafter. The circuit for energizing the winding of the start relay R230 extends from the grounded start conductor C268 by way of RA261 and the winding of R230 to battery. When energized over the above-traced circuit, the start relay R230 operates to complete, at RA231, a circuit for energizing the upper winding of the relay R225 in the C. L. R. trunk distributor 201, this circuit extending from ground at RA231 by way of RA226 and the upper winding of R225 to battery. Also, the start relay R230 interrupts, at RA233, a point in a circuit, traced hereinafter, for energizing the start relay R260 in the C. A. X. trunk distributor 202, thereby to prevent operation of the latter relay while the start relay R230 in the C. L. R. trunk distributor 201 is operated. Finally, the start relay R230 completes, at RA232, an obvious path for applying ground potential at RA232 to the start conductor C270 extending to the common start and position distributor apparatus 330.

When the relay R430 in the C. L. R. trunk circuit 400 operates to apply, at RA432, ground potential to the control conductor C451 of the C. L. R. trunk 450, this ground potential is applied to the control conductor C265. This application of ground potential to the control conductor C265 completes a circuit for energizing the upper winding of the relay R215 in the C. L. R. trunk distributor 201, this circuit extending from the grounded control conductor C265 by way of RA221 and the upper winding of R215 to battery, the relay R220 being operated at this time. When energized over the above-traced circuit, the relay R215 in the C. L. R. trunk distributor 201 operates to complete, at RA217, a circuit for energizing the lower winding thereof in series with the lower winding of the relay R225, this circuit extending from ground at the lower winding of R225 by way of the lower winding of R225, RA213, RA217 and the lower winding of R215 to battery. Also, upon operating, the relay R215 completes, at RA216, an obvious circuit for applying battery potential at the upper winding of the relay R210 to the control conductor C266 extending to the next C. L. R. trunk circuit corresponding to the C. L. R. trunk circuit associated with the C. L. R. trunk 450, thereby to assign the second C. L. R. trunk for use. Also, upon operating, the relay R215 interrupts, at RA218, a point in the holding circuit for energizing the lower winding of the relay R220 in series with the lower winding of the relay R225. The last-mentioned circuit extends, when completed, from ground at the lower winding of R225 by way of the lower winding of R225, RA218, RA222 and the lower winding of R220 to battery. When the last-mentioned holding circuit is interrupted, the relay R220 restores to interrupt, at RA222, a further point in the holding circuit for energizing the lower winding thereof, to prepare, at RA223 a holding circuit, traced hereinafter, for energizing the lower winding of the relay R210 in series with the lower winding of the relay R225, and to interrupt, at RA221, a point in the previously traced circuit for energizing the upper winding of the relay R215, the latter relay being held in its operated position at this time due to the previously traced completed holding circuit for energizing the lower winding thereof.

From the foregoing description of the operation of the C. L. R. trunk distributor 201, it will be understood that when the second C. L. R. trunk, which is at this time assigned for use, is

seized, a circuit will be completed in the C. L. R. trunk circuit associated therewith for energizing the upper winding of the relay R210 by way of the control conductor C266. When the circuit for energizing the upper winding of the relay R210 is completed, the latter relay operates to complete, at RA212, a holding circuit for energizing the lower winding thereof in series with the lower winding of the relay R225. The last-mentioned circuit extends, when completed, from ground at the lower winding of RA225 by way of the lower winding of RA225, RA223, RA212 and the lower winding of R210 to battery. Also, upon operating, the relay R210 completes, at RA211, an obvious path for applying battery potential at the upper winding of R220 to the control conductor C267, this path extending to the C. L. R. trunk circuit associated with the third C. L. R. trunk, thereby to assign the third C. L. R. trunk for use. Moreover, the relay R210 interrupts, at RA213, a point in the previously traced holding circuit for energizing the lower winding of the relay R215, thereby to cause the latter relay to restore and prepares at RA218, a point in a holding circuit, traced hereinafter, for energizing the lower winding of the relay R220 in series with the lower winding of the relay R225.

From the foregoing description of the operation of the relays R215 and R210, it will be understood that when the third C. L. R. trunk is seized, a circuit is completed for energizing the upper winding of the relay R220 by way of the control conductor C267 extending to the C. L. R. trunk circuit associated with the third C. L. R. trunk, whereupon the relay R220 is energized and operates. Upon operating, the relay R220 completes, at RA222, the previously mentioned holding circuit for energizing the lower winding thereof in series with the lower winding of the relay R225. The last-mentioned holding circuit extends from ground at the lower winding of R225 by way of the lower winding of R225, RA218, RA222 and the lower winding of R220 to battery. Also, upon operating, the relay R220 interrupts, at RA223, a point in the previously traced holding circuit for energizing the lower winding of the relay R210 and prepares, at RA221, a point in the previously traced circuit for energizing the upper winding of the relay R215 by way of the control conductor C265 extending to the C. L. R. trunk circuit 400 associated with the first C. L. R. trunk 450. At this time, if the first C. L. R. trunk is busy, the previously traced circuit for energizing the upper winding of the relay R215 is immediately completed due to the presence of ground potential upon the control conductor C265, whereupon the relay R215 immediately operates.

The relays R215, R210 and R220 in the C. L. R. trunk distributor 201 continue to interact in the above-described manner, thereby to assign the first, second and third C. L. R. trunks to be seized in the order named. It will be understood that when all of the C. L. R. trunks are busy, the relays R215, R210 and R220 continue to interact as described above until one of the C. L. R. trunks becomes idle, whereupon the idle C. L. R. trunk is assigned for use. Also, it is noted that several C. L. R. trunks are provided which are accessible to the local selector switches and which are not assigned for use by the C. L. R. trunk distributor 201. The last-mentioned C. L. R. trunks are so arranged that the local selector switches operate to seize the

last-mentioned C. L. R. trunks only in the event all of the first-mentioned C. L. R. trunks are busy. Hence, the last-mentioned C. L. R. trunks constitute overflow C. L. R. trunks.

- 5 Finally it is noted that the operation of the C. L. R. trunk distributor 201 is initially initiated prior to the operation of the relay R225 by the operation of the relay R220. Prior to the operation of the relay R225, a circuit is completed, 10 at RA227, for energizing the lower winding of the relay R220, the last-mentioned circuit extending from ground at the resistor 228 by way of the resistor 228, RA227 and the lower winding of R220 to battery. When the lower winding of the relay R220 is energized over the above-traced circuit, the latter relay operates to complete, 15 at RA222, the previously traced holding circuit for energizing the lower winding thereof in series with the lower winding of the relay R225. The relay R225 then operates to interrupt, 20 at RA227, the previously traced circuit for energizing the lower winding of the relay R220 and to prepare, at RA226, a circuit for energizing the upper winding thereof. As previously noted, 25 the circuit for energizing the upper winding of the relay R225 is completed, at RA231, upon operation of the start relay R230. Normally, the relay R225 is held in its operated position due to the completed holding circuit for energizing the lower winding thereof in series with the lower winding of one of the relays R210, 30 R215 and R220. The circuit for energizing the upper winding of the relay R225 is utilized to prevent restoration of the relay R225 during the 35 transition period when one of the relays in the group of relays R210, R215 and R220 is operating and another of the relays in this group is restoring incident to the seizure of one of the C. L. R. trunks.
- 40 Continuing now with the operation of the finder switch 700 to seize the trunk line 460 extending to the C. L. R. trunk circuit 400, when the relay R230 in the C. L. R. trunk distributor 201 operates, it completes, at RA232, an obvious 45 path for applying ground potential to the start conductor C270 extending to the common start and position distributor apparatus 330 as previously noted. This application of ground potential to the start conductor C270 causes the common start and position distributor apparatus 330 to operate and apply ground potential to one of the control conductors C1460' or C1461' in the cable 1374, depending upon whether the incoming call to the toll board is a toll or a trunk call. 50 In the present instance, the incoming call to the toll board is a trunk call. Accordingly, ground potential is applied to the control conductor C1461' in the common start and position distributor apparatus 330, thereby to complete an obvious circuit for illuminating the trunk answer lamp L1463 at the first operator position 1400. The illumination of the trunk answer lamp L1463 indicates to the operator at the first operator position 1400 that the incoming call to the toll board is a trunk call. Furthermore, the answer lamps at the first operator position are so arranged that the illumination of the trunk answer lamp L1463 identifies the trunk call as 55 being a C. L. R. trunk call.

Also, the common start and position distributor apparatus 330 operates to apply ground potential to the start conductor C1372 in the cable 1374 extending to the first operator position 1400, this operator position being previously selected by the

common start and position distributor apparatus 330 to receive the next incoming call to the toll board, as previously assumed. This application of ground potential to the start conductor C1372 completes a circuit for energizing the winding of 5 the start relay R740 in the finder switch 700. The last-mentioned circuit extends from the grounded start conductor C1372 by way of RA1311, C1375, RC1262, RA1261, the start conductor C1287 included in the cable 1286, RA1758 and the winding 10 of R740 to battery. Also, the common start and position distributor apparatus 330 marks, by way of one of the control conductors in the cable 785 and terminating in the vertical control contact bank 709 of the mechanism 701 of the finder 15 switch 700, the vertical position or level corresponding to the level in the main contact bank of the mechanism 701 wherein the group of trunks including the trunk 460 extending to the C. L. R. trunk circuit 400 terminate. In other 20 words, the common start and position distributor apparatus 330 marks the level in the main contact bank of the mechanism 701 wherein the group of C. L. R. trunks is terminated.

When energized over the previously traced circuit, the start relay R740 operates to complete, at RA742, an obvious circuit for energizing the upper winding of the electropolarized relay R710, thereby to render the latter relay exceedingly fast to operate when the intermediate winding thereof 30 is energized, as will be explained hereinafter. Also, at RA742, the start relay R740 completes a circuit for energizing the vertical magnet M733 of the mechanism 701, this circuit extending from ground at RA742 by way of RA174, RA1731, RA1722, 35 RC723 and the winding of M733 to battery. When the vertical magnet M733 is energized over the above-traced circuit, it operates to drive the wiper set of the mechanism 701 away from its normal position one step in the vertical direction. 40 Also, upon operating, the start relay R740 interrupts, at RA741, a point in a circuit, traced hereinafter, for energizing the release magnet M735 of the mechanism 701, prepares, at RA743 and RA744, a point in a circuit, traced hereinafter, for 45 energizing the supervisory relay R1230 in the relay group 1200A, and prepares, at RA746, a point in a circuit, traced hereinafter, for illuminating the supervisory lamp L761.

Also, upon operating, the vertical magnet M733 50 completes, at MA733, an obvious circuit for energizing the step relay R730, thereby to cause the latter relay to operate, and prepares, at MA733, a circuit, traced hereinafter, for energizing the lower winding of the switch-over relay R720. 55

When the wiper set of the mechanism 701 is moved away from its normal position one step in the vertical direction, the sets of switch springs S784, S785 are actuated into engagement. When the set of switch springs C784 is actuated into engagement, a holding circuit, traced hereinafter, is prepared for energizing the upper winding of the switch-over relay R720; and when the set of switch springs S785 is actuated into engagement, 60 a circuit, traced hereinafter, is prepared for energizing the release magnet M735 of the mechanism 701. 65

Upon operating, the step relay R730 interrupts, at RA731, a point in the previously traced circuit 70 for energizing the vertical magnet M733, thereby to cause the latter magnet to restore. Upon restoring, the vertical magnet M733 interrupts, at MA733, a point in the previously traced circuit 75 for energizing the step relay R730, thereby to

cause the latter relay to restore. Upon restoring, the step relay R730 recompletes, at RA731, the previously traced circuit for energizing the vertical magnet M733, thereby to cause the vertical magnet M733 to reoperate. The vertical magnet M733 and the step relay R730 interact in the above described manner, thereby to cause the vertical magnet M733 to drive the wiper set of the mechanism 701 step by step in the vertical direction until the wiper set of the mechanism 701 is driven to the vertical level wherein the trunk line 460 extending to the C. L. R. trunk circuit 400 is terminated in the main contact bank of the mechanism 701, at which time the vertical control wiper 708 engages in the associated vertical control contact bank 709 a contact terminating a control conductor in the cable 785 extending to the common start and position distributor apparatus 330 having ground potential thereon.

20 When the vertical wiper 708 engages the contact mentioned terminating a control conductor having ground potential thereon, a circuit for energizing the lower winding of the switch-over relay R720 in series with the winding of the step relay R730 is completed, this circuit extending from ground potential appearing upon the vertical wiper 708 by way of the lower winding of R720, RA725 and the winding of R730 to battery. Shortly after the relay R720 is energized over the above-traced circuit, this relay being of the slow-to-operate type, it operates to complete, at RA721, the previously mentioned holding circuit for energizing the upper winding of the switch-over relay R720, this circuit extending from ground at 35 the upper winding of R720 by way of the upper winding of R720, the set of switch springs S784, the set of switch springs S783, RA721 and the resistor 732 to battery. Also, the switch-over relay R720 interrupts, at RA725, a point in the previously traced circuit for energizing the lower winding thereof and interrupts, at RA722 and RC723, a point in the previously traced circuit for energizing the vertical magnet M733, thereby to arrest further movement of the wiper set of the mechanism 701 in the vertical direction. Furthermore, the switch-over relay R720 completes, at RA722 and RC724, a circuit for energizing the rotary magnet M734 of the mechanism 701, this circuit extending from ground at RA742 45 by way of RA714, RA731, RA722, RC724 and the winding of M734 to battery. Also, the switch-over relay R720 interrupts, at RA726 and RC728, a further point in the previously mentioned circuit for energizing the release magnet M735, prepares, at RA726 and RC727, a point in a circuit, traced hereinafter, for energizing the intermediate winding of the electropolarized relay R710, and completes, at RA729, a circuit for illuminating the supervisory lamp L768. The last-mentioned circuit extends from ground at the resistor 771 by way of the resistor 771, RA729 and L768 to battery. The illumination of the supervisory lamp L768 indicates to the operator at the first operator position 1400 that the finder-selector link illustrated is busy.

When the rotary magnet M734 is energized over the previously traced circuit, it operates to drive the wiper set of the mechanism 701 one step in the rotary direction and to complete, at MA734, a point in an obvious circuit for energizing the step relay R730, thereby to cause the latter relay to operate. Upon operating, the step relay R730 interrupts, at RA731, the previously traced circuit for energizing the rotary magnet

M734, thereby to cause the rotary magnet M734 to restore to interrupt, at MA734, the circuit for energizing the step relay R730; whereupon the step relay R730 restores to recomplete, at RA731, the previously traced circuit for energizing the rotary magnet M734. The rotary magnet M734 and the step relay R730 continue to interact, in the above described manner, until the wiper set of the mechanism 701 is rotated to the rotary position of the contact set in the main contact bank of the mechanism 701 wherein the trunk line 460 extending to the C. L. R. trunk circuit 400 is terminated; at which time the wiper 707 of the wiper set engages a contact in the contact set terminating the control conductor C462 of the trunk line 460, the last-mentioned control conductor having battery potential appearing thereon. When the wiper 707 engages the contact terminating the control conductor C462 of the trunk line 460 having battery potential appearing thereon, a circuit is completed for energizing the intermediate winding of the electropolarized relay R710, this circuit extending from ground at RA726 by way of RC727, the intermediate winding of R710, the wiper 707, the contact terminating the control conductor C462 of the trunk line 460, C462, RA431 and the winding of R420 to battery. When energized over the above-traced circuit, the electropolarized relay R710 operates exceedingly fast to complete, at RA716, a holding circuit for energizing the lower winding thereof, this circuit extending from ground at RA726 by way of RC727, RA716 and the lower winding of R710 to battery. Also, the electropolarized relay R710 prepares, at RA717, a circuit, traced hereinafter, for energizing the supervisory relay R1230 in the relay group 1200A and completes, at RA718, an obvious path for short-circuiting the intermediate winding thereof in order to reduce the resistance of the circuit for energizing the relay R420 in the C. L. R. trunk circuit 400, thereby to cause the latter relay to operate. Also, upon operating, the electropolarized relay R710 completes, at RA711 and at RA712, a connection between the line conductors C463 and C464 of the trunk line 460 and line conductors C1275 and C1276 in the cable 1286 extending to the first operator position 1400. At this time the line conductor C1180 of the trunk circuit at the first operator position is connected by way of RC1222, RA1221, C1276, RA755, RC156, RA712 and the wiper 703 to the line conductor C464 of the trunk line 460; and the line conductor C1181 of the trunk circuit at the first operator position is connected by way of RC1225, RA1224, C1275, RA752, RA753, RA711 and the wiper 702 to the line conductor C463 of the trunk line 460. Further, it is noted that the line conductors C463 and C464 of the trunk line 460 are interconnected at the repeater 410 in the C. L. R. trunk circuit 400 by way of the windings 412 and 414 thereof and the condenser 416. Moreover, the line conductors C1180 and C1181 of the trunk circuit at the first operator position are operatively associated with the winding 1107 of the talking repeater 1106 as previously explained. Accordingly, the telephone instrument at the first operator position 1400 is operatively associated with the repeater 410 in the C. L. R. trunk circuit 400.

Upon operating, the relay R420 in the C. L. R. trunk circuit 400 completes, at RA421, an obvious alternative holding circuit for energizing the winding of the relay R430, interrupts, at RA422 and RC424, a point in the previously traced path

for applying ground potential to the start conductor **C268** extending to the C. L. R trunk distributor **201**, and completes, at **RA422** and **RC423**, an obvious alternative path for applying ground potential to the control conductor **C451** of the C. L. R. trunk **450**, thereby further to insure that the C. L. R. trunk is marked as busy to the selector switches having access thereto. Finally, the relay **R420** interrupts, at **RA425**, a point in the previously mentioned circuit for returning tone current to the calling subscriber substation **T1**.

When ground potential is removed from the start conductor **C268**, the circuit for energizing the start relay **R230** in the C. L. R. trunk distributor **201** is interrupted, thereby to cause the latter relay to restore. Upon restoring, the start relay **R230** interrupts, at **RA231**, a point in the previously traced circuit for energizing the upper winding of the relay **R225**, interrupts, at **RA232**, a point in the previously mentioned path for applying ground potential to the start conductor **C270** extending from the common start and position distributor apparatus **330**, and prepares, at **RA233**, a point in the previously mentioned circuit for energizing the start relay **R260** in the C. A. X. trunk distributor **202**, thereby to render the latter distributor operative to assign C. A. X. trunks for use, as will be explained more fully herein-after.

When the path for applying ground potential to the start conductor **C270** extending into the common start and position distributor apparatus **330** is interrupted, the last-mentioned apparatus restores to remove ground potential from the start conductor **C1372** and the control conductor **C1461'** in the cable **1367** extending to the first operator position **1400**, thereby to interrupt the original circuit for energizing the start relay **R740** in the finder switch **700**, the latter relay being retained in its operated position in a manner more fully described subsequently, and to cause the trunk answer lamp **L1463** at the first operator position to be extinguished.

When the finder switch **700** operates to find the level wherein a trunk line having a calling condition thereon is terminated, the switch-over relay **R720** operates to complete, at **RA721**, a holding circuit for energizing the upper winding thereof as previously noted. Also, at **RA721**, the switch-over relay **R720** completes a path for applying battery potential to the conductor **C1461** in the cable **1286** extending to the first operator position **1400**, the last-mentioned path extending from battery at the resistor **732** by way of the resistor **732**, **RA721** and **RA751** to **C1461**. This application of battery potential to the conductor **C1461** completes an obvious path for energizing the winding of the answer pilot relay **R1260** in the relay group **1200A**, thereby to cause the latter relay to operate. Upon operating, the answer pilot relay **R1260** interrupts, at **RA1261** and **RC1262**, a point in the previously traced circuit for energizing the start relay **R740** in the finder switch **700** and completes, at **RA1261** and **RC1263**, an obvious circuit for energizing the winding of the last-mentioned relay, thereby to retain the start relay **R740** in its operated position as previously noted. Also, upon operating, the answer pilot relay **R1260** completes, at **RA1265**, the previously mentioned circuit for energizing the relay **R1140**, this circuit extending from ground at **RA1315** by way of **C1382**, **RA1265**, **C1184**, **RA1162**, **RC1163** and the winding of **R1140** to battery. Shortly after the last-men-

tioned relay is energized over the above-traced circuit, this relay being of the slow-to-operate type, operates to complete, at **RA1143**, an obvious circuit for energizing the relay **R1150**, which latter relay, being of the slow-to-operate type, operates shortly thereafter. Upon operating, the relay **R1150** completes, at **RA1154**, an obvious circuit for energizing the relay **R1160**, thereby to cause the latter relay to operate. Upon operating, the latter relay completes, at **RA1161** and **RA1162**, an obvious holding circuit for energizing the winding thereof by way of the grounded conductor **C1184** and interrupts, at **RA1162** and **RC1163**, a point in the previously traced circuit for energizing the winding of the relay **R1140**, thereby to cause the latter relay to restore and interrupt, at **RA1143**, the previously mentioned circuit for energizing the relay **R1150**, thereby to cause the latter relay to restore. Upon restoring, the relay **R1150** interrupts, at **RA1154**, the previously mentioned original circuit for energizing the relay **R1160**, which latter relay, being of the slow-to-release type, restores shortly thereafter and prepares, at **RA1162** and **RC1163**, a point in the previously traced circuit for energizing the relay **R1140**. The relay **R1140**, however, does not operate again due to the fact that ground potential has been removed from the conductor **C1184** in the interim, in a manner more fully described subsequently.

Upon operating, the relay **R1140** completes, at **RA1141** and at **RA1142**, a circuit for impressing high frequency tone upon the line conductors **C1180** and **C1181** of the trunk circuit at the first operator position **1400**, this circuit extending from ground at **RA1142** to the line conductor **C1181** and from the line conductor **C1180** by way of **RA1141**, **RA1152** and **RC1153** to the tone conductor **C1164**. The tone conductor **C1164** is connected to the ungrounded terminal of a grounded winding of a source of tone current, not shown. Also, the line conductors **C1180** and **C1181** are connected together by way of the previously traced circuit including the winding **1107** of the talking repeater **1106**, thereby to cause a tone to be produced in the receiver **1148** at the first operator position, the receiver **1148** being included in the previously traced circuit including a portion of the winding **1107** of the talking repeater **1106**.

Upon operating, the relay **R1150** interrupts, at **RA1152** and **RC1153**, a point in the previously traced circuit for impressing high frequency current upon the line conductors **C1180** and **C1181** of the trunk circuit at the first operator position and prepares, at **RA1151** and **RA1152**, an alternative path for impressing high frequency current upon the line conductors **C1180** and **C1181**. Upon operating, the relay **R1160** completes, at **RA1160**, an alternative circuit for impressing high frequency current upon the line conductors **C1180** and **C1181**. The last-mentioned circuit extends from ground at **RA1142** to the line conductor **C1181** and from the tone conductor **C1164** by way of **RA1160**, **RA1151**, **RA1152**, and **RA1141** to the line conductor **C1180**. When the relay **R1140** restores, it interrupts, at **RA1141** and at **RA1142**, points in the previously mentioned circuits for impressing high frequency current upon the line conductors **C1180** and **C1181**. Accordingly, high frequency current is impressed upon the line conductors **C1180** and **C1181** twice, thereby to cause a distinct tone or zip-zip tone to be produced in the receiver **1148** at the first operator position, thus indicating to the operator thereat

that the finder switch 700 is operating to route a call to this position.

Also, upon operating, the answer pilot relay R1260 interrupts, at RA1266, a point in the previously traced circuit for energizing the distributor start relay R1310, thereby to cause the latter relay to restore. Upon restoring, the distributor start relay R1310 interrupts, at RA1315, a point in the previously traced path for applying ground potential to the conductor C1384, thereby to prevent re-operation of the relays R1140, R1150 and R1160 in the previously described manner. Also, upon operating, the answer pilot relay R1260 completes, at RA1267, a path for applying ground potential to the start conductor C1360 included in the cable 1367 extending to the sender control circuit 300. The last-mentioned path extends from ground at RA1101 by way of RA1137, RC1138, C1187, RA1273, RA1267, C1386, RA1352, RA1322 and RA1336 to the start conductor C1360.

This application of ground potential to the start conductor C1360 extending into the sender control circuit 300 causes the apparatus included in the sender control circuit 300 to operate in a well-known manner. More particularly, the operation of the rotary switch 302 is controlled, thereby to cause the last-mentioned switch to find the cable 786 having a calling condition thereon and extending to the finder-selector link illustrated, which is being utilized to answer and extend the call as previously assumed. When the rotary switch 302 finds the cable 786, a circuit is prepared for energizing the cut-through relay R760 in the finder switch 700. Also, the operation of the rotary switch 304 is controlled, thereby to cause the last-mentioned switch to find an idle digit register and control circuit. Assuming that the rotary switch 304 selects the trunk 341 extending to the digit register and control circuit 304, the sending key set 303 at the first operator position 1400 is then in condition to be operated, thereby to cause the connection to be extended by way of the toll selector switch 800 associated with the finder switch 700 after the call has been answered at the first operator position.

Also, when the sender control circuit 300 finds the cable 786, a loop circuit for energizing the upper and lower windings of the line relay R820 in the toll selector switch 800 is completed, this circuit extending from ground in the sender control circuit 300 by way of the conductor C1790 in the cable 786, the upper winding of the line relay R820, RC813 and RA813 to the line conductor C188 of the trunk line 793, and from the line conductor C187 of the trunk line 793 by way of RA811, RC811 and the lower winding of R820 to battery, the line conductors C187 and C188 of the trunk line 793 being connected together in the sender control circuit 300 by way of the cable 786. When the above-traced loop circuit for energizing the upper and lower windings of the line relay R820 is completed, the latter relay operates to condition the toll selector switch 800 to be responsive to impulses transmitted from the digit register and control circuit 304 in a manner more fully described subsequently. At this time the calling subscriber line 962 is connected by way of the local switch train including the finder switch 471 and the selector switch 472 to the C. L. R. trunk 450 which is operatively associated with the repeater 410. Also, the telephone instrument at the first operator position 1400 is operatively associated with the talking repeater 1106. Finally, the talking repeater 1106 is operatively associated with the repeater 410

in the C. L. R. trunk circuit 400 by way of a circuit including the trunk circuit at the first operator position, the line conductors C1275 and C1276 in the cable 1286 extending between the first operator position and the finder switch 700, the finder switch 700 and the trunk line 460 extending between the finder switch 700 and the repeater 410 in the C. L. R. trunk circuit 400. Accordingly, the telephone instrument at the first operator position is operatively connected with the telephone instrument at the calling subscriber substation T1 for two-way communication therebetween. At this time the subscriber at the calling subscriber substation T1 advises the operator at the first operator position 1400 concerning the desired called party, whereupon the operator at the first operator position actuates the sending key set 303 thereat, thereby to cause the digit register and control circuit 304 to register a number of digits corresponding to the directory number of the called subscriber substation, or the directory number of a terminating exchange having access to the subscriber line extending to the called subscriber substation, which digits, when transmitted over the outgoing switch train including the selector switch 800, are effective to cause the switch train to extend the call to the destination above indicated. The exact manner of extending a call from the first operator position to various destinations will be described more fully hereinafter.

It is noted that the calling subscriber at the subscriber substation T1 has switchhook supervision after the finder switch 700 operates to find the trunk line 460 extending to the C. L. R. trunk circuit 400 and may attract the attention of the operator at the first operator position 1400 before the call is extended from the first operator position to its destination. This may be accomplished by the subscriber at the calling subscriber substation T1 merely by operating the switchhook thereat a number of times. Each time the switchhook at the subscriber substation T1 is operated, the previously traced loop circuit including the local switch train for energizing the upper and lower windings of the relay R440 in the C. L. R. trunk circuit 400 is interrupted, thereby to cause the latter relay to restore. Upon restoring, the relay R440 interrupts, at RA441 and RC443, a point in the original circuit for energizing the relay R430. However, the latter relay does not restore as the previously traced alternative holding circuit for energizing the winding thereof is completed, at RA421, due to the operated condition of the relay R420. Also, upon restoring, the relay R440 completes, at RA441 and RC442, a circuit for energizing the supervisory relay R1230 in the relay group 1200A, this circuit extending from ground at RA441 by way of RC442, RA426, the control conductor C461 of the trunk line 460, the wiper 706 of the wiper set of the mechanism 701, RA717, RA744, RA743, the conductor C1383 in the cable 1286 extending to the first operator position, RA1346, RC1348, C1384, RA1227, RC1229, the resistor 1232 and the winding of R1230 to battery. When energized over the above-traced circuit, the supervisory relay R1230 operates to complete, at RA1231, an obvious path for applying ground potential to the control conductor C1274 in the cable 1286. This application of ground potential to the control conductor C1274 completes a circuit for illuminating the supervisory lamp L767, this circuit extending from the grounded conductor C1274 by way of RA746 and L767 to battery.

Accordingly, each time the switchhook at the calling subscriber substation T1 is operated, the supervisory relay R1230 at the first operator position 1400 operates to cause the supervisory lamp 5 L767 to be illuminated. Likewise, each time the switchhook at the calling subscriber substation T1 is released, the supervisory relay R1230 restores to interrupt, at RA1231, the previously traced circuit for illuminating the supervisory 10 lamp L767. This flashing of the supervisory lamp L767 attracts the attention of the operator at the first operator position 1400, whereupon the operator at the first operator position communicates with the subscriber at the calling subscriber 15 substation T1.

Extension of a call from the switchboard to the distant exchange B

Assuming that the incoming call from the calling subscriber substation T1 is to be extended to the distant exchange B, the operator at the first operator position 1400 initiates the extension of the call by actuating the sending key set 303, as previously noted. More particularly, the operator at the first operator position operates the 20 keys of the sending key set 303, thereby to cause the digit register and control circuit 304 to register a predetermined number of digits corresponding to the directory number of the group 25 of toll lines including the toll line 340 extending to the distant exchange B. Immediately the keys of the sending key set 303 are operated, the digit register and control circuit 304 begins to operate, first to register the digits and then to control the operation of the sender control circuit 300, thereby to cause the impulses comprising the digits to be transmitted into the toll selector switch 800 in a well known manner.

Should the operator at the first operator position make an error in registering the digits, she 40 operates the error key K3 thereat, thereby to complete, at the contact 1445 of the error key K3, a circuit for energizing the error relay R1270. The last-mentioned circuit extends from ground 45 at the contact 1445 of the error key K3 by way of C1471, RA1301, C1381 and the winding of R1270 to battery. When energized over the above-traced circuit, the error relay R1270 operates to interrupt, at RA1273, a point in the previously 50 traced path for applying ground potential to the start conductor C1360 included in the cable 1367 extending to the sender control circuit 300. When ground potential is removed from the start conductor C1360, the sender control circuit 300 is released, whereupon the previously 55 traced loop circuit for energizing the line relay R820 in the toll selector switch 800 is interrupted, thereby to cause the toll selector switch 800 to be released in a manner more fully described subsequently. Shortly after operating 60 the error key K3 the operator at the first operator position releases this key, thereby to interrupt the previously traced circuit for energizing the error relay R1270. Shortly thereafter, the error relay R1270, which is of the slow-to-release 65 type, restores to recomplete, at RA1273, the previously traced path for applying ground potential to the start conductor C1360. When ground potential is reapplied to the start conductor C1360, the sender control circuit 300 operates in the previously described manner, thereby to condition the digit register and control circuit 304 to be responsive to digits set up by the operator on the sending key set 303 and to be 70 75 responsive to impulses to be transmitted thereto.

The operator at the first operator position 1400 then sets up the digits on the sending key set 303 as previously described, whereupon the digit register and control circuit 304 registers the digits and operates to cause the sender control circuit 300 to transmit the digits over the loop circuit including the line relay R820 in the selector switch 800, as previously noted.

Disregarding for the present the details of the 10 operation of the toll selector switch 800 in response to the impulses transmitted thereto from the sender control circuit 300, it is noted that when all of the digits registered in the digit register and control circuit 304 have been transmitted, the sender control circuit 300 operates to cause ground potential to be applied to the conductor C791 in the cable 786, and is then automatically released. This application of ground potential to the conductor C791 completes 15 an obvious circuit for energizing the upper winding of the cut-through relay R760. When thus energized, the cut-through relay R760 operates to complete, at RA765, a holding circuit for energizing the lower winding thereof in series with 20 the upper winding of the call pilot relay R1320. The last-mentioned circuit extends from ground at the lower winding of R760 by way of the lower winding of R760, RA765, RA751', the conductor C1460 in the cable 1286, C1369 and the upper 25 winding of R1320 to battery. When energized over the above-traced circuit, the call pilot relay R1320 operates for a purpose more fully described subsequently. Also, upon operating, the cut-through relay R760 completes, at RA764, an alternative circuit for applying ground potential 30 to the conductor C790, thereby to retain the toll selector switch 800 operated independently of the sender control circuit 300. Also, the cut-through relay R760 completes, at RA763, a circuit, 35 traced hereinafter, for illuminating the supervisory lamp L776, for a purpose more fully described subsequently, and completes, at RA766, an obvious alternative circuit for illuminating the busy lamp L768. Moreover, the cut-through 40 relay R760 completes, at RA761 and at RA762, a connection between the trunk line 793 extending to the toll selector switch 800 and the trunk circuit at the first operator position 1400.

Continuing now with the operation of the toll 45 selector switch 800, when the previously traced loop circuit including the upper and lower windings of the line relay R820 is completed due to the seizure of the cable 786 by the sender control circuit 300, the line relay R820 operates as previously explained. Upon operating, the line relay R820 50 interrupts, at RA822 and RC824, a point in a circuit, traced hereinafter, for energizing the release magnet M805 of the mechanism 801 included in the toll selector switch 800 and completes, at RA822 and RC823, a circuit for energizing the hold relay R830. The last-mentioned circuit extends from ground at RA822 by way of RA822, RC823 and the winding of R830 to battery. When energized over the above-traced circuit, the hold relay R830 55 operates to interrupt, at RA834 and RC836, a further point in the previously mentioned circuit for energizing the release magnet M805, to prepare, at RA834 and RC835, a point in a circuit, traced hereinafter, for energizing the vertical magnet M801 of the mechanism 801, and to complete, at RA833, an obvious circuit for energizing the lower winding of the electropolarized relay R810. When the lower winding of the electropolarized relay R810 60 65 70 75 80 85 90 95 98 99

is thus energized, the latter relay is rendered exceedingly fast to operate, when the upper winding thereof is energized in a manner more fully described subsequently. Also, it is noted that 5 when ground potential is applied to the control conductor C790 of the trunk line 793, a circuit is completed for energizing the upper winding of the relay R840, the latter circuit extending from the grounded control conductor C790 by way of 10 the set of switch springs S806 and the upper winding of R840 to battery. When energized over the above-traced circuit, the relay R840 operates to prepare, at RA842, a point in a holding circuit for energizing the lower winding 15 thereof, the last-mentioned circuit being interrupted at this time at RA821 due to the operated condition of the line relay R820. Also, upon operating, the relay R840 prepares, at RA843 and RC844, a point in the previously traced circuit 20 for energizing the vertical magnet M801 and interrupts, at RA849, a point in an obvious path for applying ground potential to the lower section 822 of the vertical control contact bank of the mechanism 801. The toll selector switch 800 25 is conditioned at this time to be responsive to the series of impulses transmitted thereto from the sender control circuit 300.

The subsequent operation of the toll selector switch 800 depends upon the character of the 30 first series of impulses transmitted thereto, which, in turn, depends upon the position of the desired toll or trunk line in the main contact bank of the mechanism 801. Assuming that the trunk line 320 extending between the main contact bank of the mechanism 801 and the ring-down toll line circuit 310 individually associated with the toll line 340 extending to the distant exchange B is terminated in one of the first three levels in the main contact bank of the mechanism 801, the toll 40 selector switch 800 operates as an automatic trunk hunting selector switch, only one digit being utilized to effect the operation thereof.

Each time the previously traced loop circuit 45 extending between the sender control circuit 300 and the line relay R820 in the toll selector switch 800 is interrupted, the line relay R820 restores, and each time this loop circuit is completed, the latter relay reoperates. Each time the line relay R820 restores, it interrupts, at RA822 and RC823, 50 a point in the previously traced circuit for energizing the hold relay R830 and completes, at RA822 and RC824, a point in the previously mentioned circuit for energizing the vertical magnet M801. Conversely, each time the line relay R820 operates, it interrupts, at RC822 and RC824, 55 a point in the previously mentioned circuit for energizing the vertical magnet M801 and completes, at RA822 and RC823, a point in the previously traced circuit for energizing the hold relay R830. The hold relay R830, being of the slow-to-release type, does not restore during 60 impulsing, and the vertical magnet M801 operates each time it is energized to cause the wiper set of the mechanism 801 to be driven step by step in the vertical direction. The previously mentioned 65 circuit for energizing the vertical magnet M801 extends, when completed, from ground at RA818 by way of RA822, RC824, RA834, RC835, RC859, RA858, RA843, RC844 and the winding of M801 70 to battery.

When the wiper set of the mechanism 801 is driven away from its normal position one step in the vertical direction, the sets of switch springs S806 and S898 are actuated into disengagement 75 and engagement, respectively. When the set of

switch springs S806 is actuated into disengagement, the previously traced circuit for energizing the upper winding of the relay R840 is interrupted; and when the set of switch springs S898 is actuated into engagement, an additional point 5 in the previously mentioned circuit for energizing the release magnet M805 is prepared. Also, each time the line relay R820 restores, it completes, at RA821, a point in the previously mentioned holding circuit for energizing the lower winding of 10 the relay R840, the last-mentioned holding circuit extending from ground at RA833 by way of RA821, RA842 and the lower winding of R840 to battery. The relay R840, being of the slow-to-release type, remains operated during impulsing 15 due to the fact that the holding circuit for energizing the lower winding thereof is intermittently completed. At the conclusion of the first digit the wiper set of the mechanism 801 occupies 20 a vertical position wherein the vertical control contact 807 engages one of the contacts in the lower section 822 of the vertical control contact bank, thereby to prepare a circuit, traced hereinafter, for energizing the relay R885. Also, when the wiper set of the mechanism 801 occupies 25 the vertical position noted, the set of switch springs S810 is actuated, thereby to open the contact 812 thereof and to close the contact 811 thereof in order to prepare an additional point in the previously mentioned circuit for energizing the relay R885. 30

At the conclusion of the first digit mentioned, the line relay R820 reoperates over the previously traced loop circuit extending into the sender control circuit 300, whereupon the previously traced 35 holding circuit for energizing the lower winding of the relay R840 is interrupted. Shortly thereafter, the relay R840, being of the slow-to-release type, restores to interrupt, at RA842, an additional point in the previously traced holding 40 circuit for energizing the lower winding thereof, to interrupt, at RA843 and RC844, a point in the previously traced circuit for energizing the vertical magnet M801, and to complete, at RA849, 45 the previously mentioned circuit for energizing the relay R885. The last-mentioned circuit extends from ground at RA849 by way of the lower section 822 of the vertical control contact bank, the associated vertical control wiper 807, the contact 811 of the set of switch springs S810, and the 50 winding of R885 to battery. When energized over the above-traced circuit, the relay R885 operates to complete, at RA886, an obvious circuit for energizing the relay R870, thereby to cause the latter relay to operate. Also, upon operating, the relay R885 completes, at RA881, an obvious circuit for energizing the lower winding of the relay R890 in series with the winding of the relay R850, thereby to cause the latter relays to 55 operate. Upon operating, the relay R870 prepares, at RA872, a holding circuit, traced hereinafter, for energizing the winding thereof and completes, at RA873, a circuit for energizing the lower winding of the relay R860. The last-mentioned circuit extends from ground at RA833 by 60 way of C890, MA804, the contact 897 of the set of switch springs S895, RA873, RA885 and the lower winding of R860 to battery. When energized over the above-traced circuit, the relay R860 operates to prepare, at RA865 and RC866, 65 a point in a circuit, traced hereinafter, for energizing the rotary magnet M802 of the switching mechanism 801. Also, upon operating, the relay R870 prepares, at RA878, a point in the previously mentioned circuit for energizing the ro- 70 75

tary magnet M802. Upon operating, the relay R850 completes, at RA855, and at RA856 and RA857, a holding circuit for energizing the lower winding thereof, this circuit extending from ground at RA833 by way of C890, RA856, RA851, RA855 and the winding of R850 to battery. Also, upon operating, the relay R850 completes, at RA855 and at RA856 and RA857, a path for short-circuiting the lower winding of the relay R890, thereby to cause the latter relay to restore. This path extends from ground at RA833 by way of C890, RA856, RA857, RA855, the lower winding of R890 and RA887 to ground. Moreover, upon operating, the relay R850 completes, at RA851, a holding circuit for energizing the relay R870, the last-mentioned circuit extending from ground at RA833 by way of C890, RA851, MA803, RA872, RC884, RA883 and the winding of R870 to battery. Finally, upon operating, the relay R850 completes, at RA858 and RC858, at RA851' and RC852', and at RA854' and RC855', the previously mentioned circuit for energizing the rotary magnet M802. The last-mentioned circuit extends from ground at RA833 by way of C890, RA846, RC848, RC858, RA858, RA843, RC845, RA851', RC852', RC866, RA865, RA854', RC855', RA878, RC817 and the winding of M802 to battery.

When energized over the above-traced circuit, the rotary magnet M802 operates to drive the wiper set of the mechanism 801 one step in the radial direction, whereupon the vertical control wiper 807 disengages the lower section 822 of the vertical control contact bank. Also, upon operating, the rotary magnet M802 interrupts, at MA803, a point in the previously traced holding circuit for energizing the relay R870 and interrupts, at MA804, a point in the previously traced circuit for energizing the lower winding of the relay R860. The relay R860 restores immediately. However, the relay R870, being of the slow-to-release type, does not immediately restore. Upon restoring, the relay R860 interrupts, at RA865 and RC866, a point in the previously traced circuit for energizing the rotary magnet M802, thereby to cause the rotary magnet M802 to restore. Upon restoring, the rotary magnet M802 recompletes, at RA803, the previously traced holding circuit for energizing the winding of the relay R870 and recompletes, at MA803, the previously traced circuit for energizing the lower winding of the relay R860, thereby to cause the latter relay to re-operate. Upon reoperating, the relay R860 recompletes, at RA865 and RC866, the previously traced circuit for energizing the rotary magnet M802, thereby to cause the rotary magnet to re-operate. The rotary magnet M802 and the relay R860 interact, in the above-described manner, thereby to cause the wiper set of the mechanism 801 to be rotated step by step in the rotary direction until an idle trunk line in the group of trunk lines extending to the toll line circuits associated with the toll lines extending to the distant exchange B is found.

Each time the wiper set of the mechanism 801 is rotated one step in the rotary direction, a trunk line is tested by the electropolarized relay R810. In the event the trunk line is busy, ground potential appears upon the control conductor thereof, thereby completing a path for short-circuiting the upper winding of the electropolarized relay R810, this path extending from the grounded control conductor C790 of the trunk line 793 by way of the upper winding of R810, RA832, RC882, RA881 and the wiper 805 of the wiper set of the

mechanism 801 to the grounded control conductor of the busy trunk line. When an idle trunk line is tested by the electropolarized relay R810 in the above-described manner, battery potential appears upon the control conductor thereof, thereby to complete a circuit substantially identical to the above-traced circuit for energizing the upper winding of the electropolarized relay R810. When the upper winding of the electropolarized relay R810 is thus energized, the electropolarized relay R810 operates exceedingly fast to complete, at RA816, a holding circuit for energizing the intermediate winding thereof, the last-mentioned circuit extending from the grounded control conductor C790 of the trunk line 793 by way of RA816 and the intermediate winding of R810 to battery. Also, upon operating, the electropolarized relay R810 interrupts, at RA817, a point in the previously traced circuit for energizing the rotary magnet M802, thereby to prevent further movement of the wiper set of the mechanism 801 in the rotary direction and interrupts, at RA818, a point in the previously traced circuit for energizing the hold relay R830, thereby to cause the latter relay to restore shortly thereafter. Moreover, the electropolarized relay R810 interrupts, at RA811 and RC811 and at RA813 and RC813, points in the previously traced loop circuit for energizing the upper and lower windings of the line relay R820, thereby to cause the line relay R820 to restore. Also, the electropolarized relay R810 prepares, at RA811 and RC812 and at RA813 and RC814, points in a circuit, traced hereinafter, for connecting the line conductors C187 and C188 of the trunk line 793 to the line conductors of the seized trunk line. Finally, the electropolarized relay R810 completes, at RA815, a path for applying ground potential to the wiper 805 of the wiper set of the mechanism 801, the last-mentioned path extending from ground at RA815 by way of RC882 and RA881 to the wiper 805.

This application of ground potential to the wiper 805 of the wiper set of the mechanism 801 causes the line circuit associated with the seized trunk line to operate and mark the associated trunk line as busy to the switches having access thereto. Assuming that the trunk line 320 extending to the ring-down toll line circuit 310 individually associated with the toll line 340 extending to the distant exchange B is seized by the toll selector switch 800, the ring-down toll line circuit 310 operates at this time, thereby to mark the toll line 340 as busy to the switches having access thereto.

Shortly after the electropolarized relay R810 operates to interrupt, at RA818, the previously traced circuit for energizing the hold relay R830, the latter relay restores to interrupt, at RA833, points in the previously traced holding circuits for energizing the relays R850 and R870 and in the previously traced circuit for energizing the lower winding of the relay R860, thereby to cause the latter relays to restore.

Also, it is noted that prior to the restoration of the relays R850 and R830, battery through the resistor 827 was connected to the control conductor C789 of the trunk line 793 extending by way of the cable 786 to the sender control circuit 300 and that this circuit is, at this time, interrupted, at RA831 and at RA850, upon the restoration of the relays R830 and R850, respectively. The connection of battery potential by way of the resistor 827 to the control conductor C789 is effective to prevent the sender control circuit 300 from transmitting additional series of impulses

comprising a second digit to the toll selector switch 800 until the toll selector switch 800 is completely operated to find an idle toll line extending to the distant exchange B.

5 In the event the distant exchange B is of the automatic type, series of impulses are transmitted from the sender control circuit 300 by way of the toll selector switch 800, the ring-down toll line circuit 310 and the toll line 340 thereto, 10 thereby to cause the switch train therein to operate and extend the connection to a toll operator position in the distant exchange B. In the interim, during the time the toll selector switch 800 is operating to find an idle toll line 15 extending to the distant exchange B, battery potential is applied by way of the resistor 827 to the control conductor C789, thereby to cause the sender control circuit 300 to store the digits until an idle toll line extending to the distant 20 exchange B is found, as previously noted.

When the toll selector switch 800 operates to seize the trunk line 320 extending to the ring-down toll line circuit 310, the wiper 804 in the 25 contact bank of the mechanism 801 terminates a control conductor of the trunk line 320 which is adapted to have ground potential in the ring-down toll line circuit 310 applied thereto, thereby to complete a circuit, traced hereinafter, for 30 illuminating the supervisory lamp L776. Also, when the toll selector switch 800 operates as previously described, the relay R870 restores, thereby to prepare, at RA871, a further point in the previously mentioned circuit for illuminating 35 the supervisory lamp L776.

At this time the trunk circuit at the first operator position 1400 is connected to the toll line 340, the line conductor C1180 of the trunk circuit at the first operator position being connected 40 by way of RC1212, RA1211, the conductor C1278 in the cable 1286, RA754, RA762, C788, RA813, RC814 and RA893 to the wiper 803 of the wiper set of the mechanism 801; and the line conductor C1181 of the trunk circuit at the first operator 45 position being connected by way of RC1215, RA1214, the conductor C1277 in the cable 1286, RA751, RA761, C787, RA811, RC812, RA860 and RA891 to the wiper 802 of the wiper set of the mechanism 801. Also, the line conductors 50 C1180 and C1181 of the trunk circuit at the first operator position are operatively associated with the talking repeater 1106 as previously explained; and the wipers 802 and 803 of the wiper set of the mechanism 801 engage the line conductors of 55 the trunk line 320 extending to the ring-down toll line circuit 310 individually associated with the toll line 340 extending to the distant exchange B, thereby operatively connecting the first operator position 1400 with the distant exchange B.

60 The operator at the first operator position 1400 then causes ringing current to be projected over the toll line 340 extending to the distant exchange B, this being accomplished by operating the ring key K5 at her position to its front position. When 65 the ring key K5 is thus operated, an obvious circuit is completed at the contact 1405 for energizing the front split relay R1210, thereby to cause the latter relay to operate. Also, at the contact 1408 of the ring key K5 an obvious path is completed for applying battery potential at the resistor 1409 to the control conductor C1466. Finally, at the contact 1407 of the ring key K5 an obvious path for applying ground potential to the control conductor C1469 is completed; and at the 70 75 contact 1406 of the ring key K5 an obvious path

is completed for applying alternating ringing current to the control conductor C1468.

Upon operating, the front split relay R1210 disconnects, at RA1211 and RC1212 and at RA1214 and RC1215, the conductors C1278 and C1277, respectively, included in the cable 1286 from the line conductors C1180 and C1181, respectively, of the trunk circuit at the first operator position; and connects, at RA1211 and RC1213 and at RA1214 and RC1216, the conductors C1278 and C1277, respectively, to the control conductors C1468 and C1469, thereby to cause alternating ringing current to be projected over the conductors C1278 and C1277. In view of the fact that the last-mentioned conductors are connected by 15 way of the trunk line 793 in the toll selector switch 800 to the trunk line 320 and the toll line 340, alternating ringing current is projected over the toll line 340 to the distant exchange B. Also, upon operating, the front split relay R1210 prepares, at RA1217 and RC1218, a further point in the previously mentioned circuit for illuminating the supervisory lamp L776.

The alternating ringing current projected over the trunk line 320 causes the ring-down toll line 25 circuit 310 to operate and apply ground potential to the control conductor of the trunk line 320 terminated by the contact in the main contact bank of the mechanism 801 engaged by the wiper 804 of the wiper set of the mechanism 801, 30 thereby to complete a circuit for illuminating the supervisory lamp L776. The last-mentioned circuit extends from the grounded control conductors of the trunk line 320 by way of the wiper 804 of the wiper set of the mechanism 801, RA871, the 35 control conductor C789 of the trunk line 793, RA763, the supervisory lamp L776, the contact 774 of the talk key 780, the conductor C1284 in the cable 1286, RA1217, RC1218, C1466, the contact 1408 of the ring key K5, and the resistor 40 1409 to battery. When the above-traced circuit is completed, the supervisory lamp L776 is illuminated, thereby to indicate to the operator at the first operator position that the ring-down toll line circuit 310 individually associated with the toll line 340 has been rung down and that alternating ringing current is being projected over the toll line 340 to the distant exchange B.

After the operator at the first operator position 50 operates the ring key K5 to its front position, thereby to cause alternating ringing current to be projected over the toll line 340 extending to the distant exchange B, she restores the ring key K5 to its normal position. When the ring key K5 is restored to its normal position, the previously traced path for applying alternating ringing current to the control conductors C1468 and C1469 is interrupted at the contacts 1406 and 1407. Also, at the contact 1405 of the ring key K5 the previously mentioned circuit 55 for energizing the front split relay R1210 is interrupted; and at the contact 1408 of the ring key K5 the previously traced circuit for illuminating the supervisory lamp L776 is interrupted, thereby to cause the supervisory lamp L776 to be 60 extinguished. Shortly after the previously mentioned circuit for energizing the front split relay R1210 is interrupted, the latter relay restores, this relay being of the slow-to-release 65 type, thereby to disconnect, at RA1211 and RC1213 and at RA1214 and RC1216, the conductors C1277 and C1278 in the cable 1286 from the control conductors C1469 and C1468, respectively. Also, at RA1211 and RC1212 and at RA1214 and RC1215, the conductors C1278 and 70 75

C1277 are respectively connected to the line conductors C1180 and C1181 of the trunk circuit at the first operator position, thereby operatively to associate the toll line 340 extending to the distant exchange B with the first operator position. 5 Also, upon restoring, the front split relay R1210 interrupts, at RA1217 and RC1218, a further point in the previously traced circuit for illuminating the supervisory lamp L776 and prepares, at RA1217 and RC1219, a point in a circuit, traced hereinafter, for energizing the relay R1120 in the relay group 1200A.

When the ring key K5 is returned to its normal position, battery potential at the contact 1408 thereof is removed from the control conductor C1466 as previously noted, thereby to cause the supervisory lamp L776 to be extinguished and to cause the ring-down toll line circuit 310 to operate and remove ground potential from the control conductor thereof which is terminated in the main contact bank of the mechanism 801 of the toll selector switch 800 engaged by the wiper 804 of the wiper set of the mechanism 801. Accordingly, when the front split relay R1210 restores, the previously mentioned circuit for energizing the relay R1120 is not immediately completed.

At this time the operator at the first operator position 1400 in the central office A may communicate with the toll operator in the distant exchange B, the toll operator position in the distant exchange B being connected by way of the toll line 340, the ring-down toll line circuit 310, the trunk line 320, the toll selector switch 800 and the conductors C1277 and C1278 in the cable 1286 30 to the line conductors C1181 and C1180 of the trunk circuit at the first operator position. The operator at the first operator position 1400 in the central office A then instructs the operator at the toll operator position in the distant exchange 35 B concerning the forwarding of the call.

After the call has been forwarded by the operator at the toll operator position in the distant exchange B and the operator at the first operator position 1400 in the central office A has verified the forwarding of the call, the operator at the first operator position informs the subscriber at the calling substation T1 that he may begin the conversation. The operator at the first operator position then restores the talk key 780 40 of the finder switch 700 to its normal position. When the talk key 780 is returned to its normal position, the previously mentioned circuit for illuminating the supervisory lamp L776 and for energizing the relay R1120 in series is interrupted at the contact 774 thereof. However, an alternative circuit, traced hereinafter, is prepared at the contact 775 of the talk key 780 for illuminating the supervisory lamp L776. Also, when 45 the talk key 780 is restored to its normal position, a further point in the previously traced circuit for energizing the lower winding of the connect relay R750 is interrupted at the contact 782 thereof; and a point is interrupted at the contact 781 of the talk key 780 in the previously traced holding circuit for energizing the upper winding of the connect relay R750 in series with the talk relay R1130, thereby to cause the latter 50 relays to restore.

Upon restoring, the connect relay R750 55 interrupts, at RA752 and RA753 and at RA755 and RA756, points in the previously traced circuit for connecting the C. L. R. trunk 450 to the trunk circuit at the first operator position and interrupts, at RA751 and at RA754, points in the previously

traced circuit for connecting the called toll line 340 to the trunk circuit at the first operator position 1400. Also, at RA753 and RC753 and at RA756 and RC754 a direct connection is completed between the finder switch 700 and the trunk line 783 extending between the finder switch 700 and the toll selector switch 800, thereby to complete a direction connection between the C. L. R. trunk 450 and the toll line 340. Also, at this time, the calling subscriber line 962 is operatively connected to the C. L. R. trunk 450 by way of the local switch train including the finder switch 471 and the selector switch 472, and the called subscriber is operatively connected with the toll line 340 by way of the toll operator position in the 15 distant exchange B. Hence, at this time, the subscribers at the calling and called substations may communicate with each other.

Also, upon restoring, the connect relay R750 20 interrupts, at RA751 and at RA757, points in the previously traced circuits for respectively energizing the call pilot relay R1320 and the answer pilot relay R1260, thereby to cause the latter relays to restore. Moreover, the connect relay R750 25 interrupts, at RA758, a point in the previously traced circuit for energizing the start relay R740, thereby to cause the latter relay to restore. Upon restoring, the start relay R740 30 interrupts, at RA742, a point in the previously mentioned circuit for energizing the upper winding of the electropolarized relay R710, interrupts, at RA743 and RA744, an additional point in the previously traced circuit for energizing the supervisory relay R1230, and prepares, at RA744 and 35 RC745, a point in an alternative circuit, traced hereinafter, for illuminating the supervisory lamp L767. Finally, the start relay R740 40 interrupts, at RA746, a further point in the previously traced circuit for illuminating the supervisory lamp L767 and prepares, at RA747, a point in the 45 previously mentioned circuit for energizing the release magnet M735. At this time the switch-over relay R720 remains in its operated condition due to the completed holding circuit for energizing the upper winding thereof; the electropolarized relay R710 50 remains in its operated condition due to the completed holding circuit for energizing the intermediate winding thereof; and the cut-through relay R760 remains in its operated condition due to the completed holding circuit for energizing the lower winding thereof.

At this time the subscriber at the calling substation T1 has switchhook supervision and may attract the attention of the operator at the first operator position 1400 by operating the switchhook at the substation T1 a number of times, thereby to cause the relay R440 in the C. L. R. trunk circuit 400 to operate and restore intermittently as previously explained. Each time the relay R440 restores, it completes, at RA441 and 60 RC442, the previously mentioned alternative circuit for illuminating the supervisory lamp L767, this circuit extending from ground at RA441 by way of RC442, RA442, the control conductor C461 of the trunk line 460, the wiper 706 of the wiper set of the mechanism 701 of the finder switch 700, RA717, RA744, RC745 and the supervisory lamp L767 to battery. Conversely, each time the relay R440 operates, it interrupts, at RA441 and 65 RC442, a point in the previously traced alternative circuit for illuminating the supervisory lamp L767. Accordingly, the subscriber at the calling substation T1 may cause the supervisory lamp L767 to flash, thereby to attract the attention of the operator at the first operator position 1400. 70

Upon restoring, the talk relay R1130 in the relay group 1200A at the first operator position 1400 interrupts, at RA1132 and RC1133 and at RA1134 and RC1135, points in the previously traced circuit for connecting the trunk circuit thereat to the talking repeater 1106 and completes, at RA1132 and RC1132 and at RA1134 and RC1134, points in the previously traced circuit for connecting the trunk circuit at the first operator position to the monitoring repeater 1102. Also, upon restoring, the talk relay R1130 completes, at RA1131, the previously mentioned path for applying ground potential to the control conductor C1166 of the trunk line 1165 extending to the chief operator position, thereby to indicate to the chief operator that the operator at the first operator position is not now engaged in setting up a connection. Finally, upon restoring, the talk relay R1130 interrupts, at RA1131 and RC1138, a point in the previously traced circuit for applying ground potential to the start conductor C1360 included in the cable 1367 extending to the sender control circuit 300 and completes, at RA1131 and RC1139, a point in the previously traced path for applying ground potential to the conductor C1285 included in the cable 1286. Upon restoring, the answer pilot relay R1260 interrupts, at RA1267, a further point in the previously traced path for applying ground potential to the start conductor C1360 included in the cable 1367 extending to the sender control circuit 300 and prepares, at RA1266, a point in the previously traced circuit for energizing the distributor start relay R1310. Upon restoring, the call pilot relay R1320 prepares, at RA1321, a further point in the previously traced circuit for energizing the distributor start relay R1310 and prepares, at RA1322, a point in the previously traced path for applying ground potential to the start conductor C1360 included in the cable 1367 extending to the sender control circuit 300. At this time the relay group 1200A at the first operator position 1400 is completely released for further use and the operator at this position may receive other calls by operating the talk or link listening key of an idle finder-selector link away from its normal position in the manner previously explained.

In the above description of the operation of the toll selector switch 800 to find an idle trunk line in the group of trunk lines including the trunk line 320 extending to the ring-down toll line circuits associated with the group of toll lines extending between the central office A and the distant exchange B, it was assumed that the trunk line 320 in this group was idle at this time and that the toll selector switch 800 operated to seize the trunk line 320. However, it may occur that all of the trunk lines in the group of trunk lines including the trunk line 320 are busy at this time due to the fact that all of the toll lines extending between the central office A and the distant exchange B are busy. Accordingly, at this time the toll selector switch 800 continues to operate until the wiper set of the mechanism 801 thereof is driven in the rotary direction to the position of the contact set in the main contact bank of the mechanism 801 wherein the last busy trunk line in the group of trunk lines including the trunk line 320 is terminated. At this time ground potential appears upon the contact of the contact set in the main contact bank of the mechanism 801 engaged by the wiper 806 of the wiper set of the mechanism 801. This application of ground potential to the wiper 806 of the wiper set of the mechanism 801 completes a circuit for energizing the upper winding of the relay R860

in the toll selector switch 800, this circuit extending from the grounded wiper 806 by way of RA874, RA875, RA853, RC857' and the upper winding of R860 to battery. Accordingly, the operation of the rotary magnet M802 to interrupt, at RA804, the previously traced holding circuit for energizing the lower winding of the relay R860 does not cause the relay R860 to restore due to the above-traced completed circuit for energizing the upper winding thereof. Hence the relay R860 does not restore to interrupt, at RA865 and RC866, the previously traced circuit for energizing the rotary magnet M802. Accordingly, the rotary magnet M802 remains in its operated position at this time. The operated rotary magnet M802 interrupts, at RA803, a point in the previously traced holding circuit for energizing the relay R870, thereby to cause the latter relay, which is of the slow-to-release type, to restore shortly thereafter.

Upon restoring, the relay R870 interrupts, at RA874 and RA875, a point in the previously traced circuit for energizing the upper winding of the relay R860 and completes, at RA875 and RC876, and alternative circuit for energizing the upper winding of the relay R860, the last-mentioned circuit extending from ground at RA833 by way of C890, RA846, RC848, RC858, RA858, RA843, RC845, RA851', RC852', RC876, RA875, RA853, RC857' and the upper winding of R860 to battery. Also, upon restoring, the relay R870 completes, at RA877, a circuit for energizing the intermediate winding of the electropolarized relay R810 in series with the relay R890, the last-mentioned circuit extending from ground at RA833 by way of C890, the upper winding of R890, RA877, RA864 and the intermediate winding of R10 to battery. When energized over the above-traced circuit, the electropolarized relay R10 operates to interrupt, at RA811 and RC811 and at RA813 and RC813, points in the previously traced circuit for energizing the upper and lower windings of the line relay R20 in series, thereby to cause the latter relay to restore. Upon restoring, the line relay R20 interrupts, at RA822 and RC823, the previously traced circuit for energizing the winding of the hold relay R830, thereby to cause the latter relay to restore.

Also, upon operating, the electropolarized relay R810 completes, at RA816, the previously traced holding circuit for energizing the intermediate winding thereof, this circuit extending from the grounded control conductor C790 of the trunk line 193 by way of RA816 and the intermediate winding of R810 to battery. Also, at RA816, the electropolarized relay R810 completes a holding circuit for retaining the relays R850, R860 and R890 in their operated positions, this holding circuit extending from the grounded control conductor C790 of the trunk line 193 by way of RA816, RA864, RA877 and the upper winding of R890 to the conductor C890, from the conductor C890 by way of RA856, RA857, RA855 and the winding of R850 to battery, and from the conductor C890 by way of RA846, RC848, RC858, RA858, RA843, RC845, RA851', RC852', RC876, RA875, RA853, RC857' and the upper winding of R860 to battery.

Accordingly, at this time the electropolarized relay R810 and the relays R850, R860 and R890 remain in their operated positions, the remainder of the relays being restored. Further, it is noted that, upon operating, the electropolarized relay R810 interrupts, at RA818, a point in the previously traced circuit for energizing the release

magnet M805 of the mechanism 801. Accordingly, the wiper set of the mechanism 801 is not released at this time. Also, it is noted that when the relay R870 restores, it prepares, at RA871, a point in a path traced hereinafter for applying interrupted ground potential to the control conductor C789 of the trunk line 793, the last-mentioned path being completed, at RA892, upon operation of the relay R890. The path for applying interrupted ground potential to the control conductor C789 of the trunk line 793 extends from the conductor C809 having interrupted ground potential applied thereby by way of RA892 and RA871 to the control conductor C789 of the trunk line 793. This application of interrupted ground potential to the control conductor C789 of the trunk line 793 completes the previously traced circuit for energizing the winding of the relay R1120 in the relay group 1200A subsequent to the operation of the cut-through relay R760 in the finder switch 700, thereby to cause the relay R1120 to operate intermittently and short-circuit intermittently the resistor 1122. Each time the resistor 1122 is thus short-circuited, the supervisory lamp L776 is illuminated. Hence, the supervisory lamp L776 flashes, thereby to indicate to the operator at the first operator position that all of the toll lines in the group of toll lines including the toll line 340 extending between the central office A and the distant exchange B are busy at this time. Also, it is noted that when the hold relay R830 restores, the previously traced path for applying battery potential at the resistor 827 to the control conductor C789 of the trunk line 793 is interrupted, at RA831, thereby to permit the sender control circuit 300 to operate and transmit the impulses comprising the remainder of the digits to the toll selector switch 800. However, these impulses are not transmitted over the last trunk line in the group of trunk lines including the trunk line 320 due to the fact that, upon operating, the relay R890 interrupts, at RA891 and RA893, the connection between the line conductors C787 and C788 of the trunk line 793 extending to the toll selector switch 800 and the wipers 802 and 803 of the wiper set of the mechanism 801 in the toll selector switch 800. When the sender control circuit 300 transmits all of the impulses comprising the digits which have been registered in the digit register and control circuit 304, it operates to cause ground potential to be applied to the control conductor C791 in the cable 786 in order to complete the previously traced circuit for energizing the upper winding of the cut-through relay R760, as previously explained. Also, when the sender control circuit transmits all of the digits registered it is automatically released. The cut-through relay R760 then operates to complete, at RA763, the previously mentioned circuit for energizing the relay R1120 in the relay group 1200A and for illuminating the supervisory lamp L776 as previously explained. The operator at the first operator position 1400 then advises the calling party that the desired connection cannot immediately be had due to the fact that all of the toll lines extending from the central office A to the distant exchange B are busy at this time. The operator at the first operator position then releases the toll selector switch 800 in a manner more fully described subsequently.

An established connection routed by way of one of the finder-selector links individually associated with the first operator position 1400 may

be monitored by the operator thereat. For example, in order to monitor the established connection routed by way of the finder-selector link illustrated associated with the first operator position 1400, the operator thereat operates the monitor key 770 of the finder switch 700 away from its normal position. When the monitor key 770 is operated away from its normal position, a circuit is completed, at the contact 773 thereof, for energizing the monitor relay R1110 in the relay group 1200A, this circuit extending from ground at the contact 773 of monitor key 770 by way of the contact 773, the conductor C1282 in the cable 1286, RA1125, RC1125, C1282', RA1136 and the winding of R1110 to battery. When energized over the above-traced circuit, the monitor relay R1110 operates to complete, at RA1115 and RC1117 and at RA1118 and RC1119, a circuit for operatively associating the receiver 1148 of the telephone instrument at the first operator position with the monitoring repeater 1102. The last-mentioned circuit extends from the receiver 1148 by way of the plug tip 1123, the jack tip 1125, C1172, RA1118, RC1119, the winding 1104 of the monitoring repeater 1102, RA1117, RA1105, C1173, the jack tip 1158 and the plug tip 1156 to the receiver 1148. Also, at RA1112 and RC1114, the monitor relay R1110 completes a connection between the line conductor C1167 of the trunk line 1165 and one terminal of the winding 1104 of the monitoring repeater 1102. Accordingly, the line conductors C1168 and C1167 of the trunk line 1165 extending to the chief operator position are operatively associated with the winding 1104 of the monitoring repeater 1102. Finally, at RA1111, the monitor relay R1110 interrupts a point in the previously traced path for applying ground potential to the control conductor C1166 of the trunk line 1165. When ground potential is removed from the control conductor C1166 of the trunk line 1165, the signal device at the chief operator position is operated, thereby to indicate to the chief operator that the operator at the first operator position 1400 is busy.

Also, when the monitor key 770 is operated, the conductors C1280 and C1281 in the cable 1286 are respectively connected, at the contacts 772 and 771 of the monitor key 770, to the line conductors C787 and C788, respectively, of the trunk line 793 extending between the finderswitch 700 and the toll selector switch 800. Also, it is noted that the conductor C1280 in the cable 1286 is connected to the line conductor C1180; and the conductor C1281 in the cable 1286 is connected to the line conductor C1181, the line conductors C1180 and C1181 of the trunk circuit at the first operator position being operatively associated with the monitoring repeater 1102 as previously explained. Accordingly, at this time the operator at the first operator position may monitor the established connection routed between the calling substation T1 and the called substation in the distant exchange B by way of the finder-selector link illustrated. Moreover, it is noted that at this time the chief operator may monitor this established connection by way of the trunk line 1165.

In order to interrupt the monitoring connection between the first operator position 1400 and the established connection routed by way of the

finder-selector link illustrated, the operator at the first operator position restores the monitor key 770 of the finder switch 700 to its normal position. When the monitor key 770 is restored to its normal position, the previously traced circuit for energizing the monitor relay R1110 is interrupted at the contact 773 thereof. Also, at the contacts 771 and 772 of the monitor key 770, the conductors C1181 and C1180 in the cable 1286 are disconnected from the conductors C787 and C788, respectively, of the trunk line 793 extending between the finder switch 700 and the toll selector switch 800. When the previously traced circuit for energizing the monitor relay R1110 is interrupted, the latter relay restores to interrupt, at RA1115 and RC1117 and at RA1118 and RC1119, the previously traced connection between the receiver 1148 at the first operator position 1400 and the monitoring repeater 1102. Also, the monitor relay R1110 interrupts, at RA1112 and RC1114, the previously traced connection between the trunk line 1163 extending to the chief operator position and the monitoring repeater 1102 at the first operator position, completes, at RA1112 and RC1113 and at RA1118 and RC1118, the previously mentioned connection between the trunk line 1165 and the talking repeater 1106 at the first operator position, and completes, at RA1111, the previously traced path for applying ground potential to the control conductor C1166 of the trunk line 1165. This application of ground potential to the control conductor C1166 of the trunk line 1165 operates a signal at the chief operator position, thereby to indicate to the chief operator that the operator at the first operator position is not engaged in setting up a connection thereat.

Also, it is noted that an established connection routed by way of one of the finder-selector links individually associated with the first operator position 1400 may be split in either direction. For example, the operator at the first operator position may wish to split the established connection routed by way of the finder-selector link illustrated and talk to the calling party to the exclusion of the called party. This is accomplished by operating the talk key 780 of the finder switch 700 to its operated position, thereby to cause the connect and start relays R750 and R740 in the finder switch 700 to operate as previously explained. Also, when the talk key 780 is operated to its operated position, the talk relay R1130, the answer pilot relay R1260 and the call pilot relay R1320 are reoperated, as previously explained.

The operator at the first operator position 1400 then operates the cut-off key K6 to its rear position, thereby to complete, at the contact 1441 thereof, a circuit for energizing the front split relay R1210, the last-mentioned circuit extending from ground at the contact 1441 of the cut-off key K6 by way of the conductor C1467 and the winding of R1210 to battery. When energized over the above-traced circuit, the front split relay R1210 operates, as previously explained, thereby to disconnect, at RA1211 and RC1212 and at RA1214 and RC1215, the conductors C1278 and C1277 included in the cable 1286 from the trunk circuit at the first operator position. Also, upon operating, the front split relay R1210 interrupts, at RA1217 and RC1219, a point in the previously mentioned circuit for energizing the relay R1120 and for illuminating the supervisory lamp L776. At this time the conductors C1275 and C1276 are connected to the trunk circuit

at the first operator position and by way of the finder switch 700 to the trunk line 460; and the conductors C1278 and C1277, which are connected to the line conductors of the trunk line 793 extending to the toll selector switch 800, are disconnected from the trunk circuit at the first operator position. Accordingly, at this time, the operator at the first operator position may talk to the party at the calling substation T1 to the exclusion of the called party in the distant exchange B. After the operator at the first operator position has finished her conversation with the calling party at the substation T1, the cut-off key K6 is returned to its normal position, thereby to interrupt, at the contact 1441 thereof, the previously traced circuit for energizing the front split relay R1210, whereupon the latter relay, being of the slow-to-release type, restores shortly thereafter to reconnect the conductors C1277 and C1278 in the cable 1286 to the trunk circuit at the first operator position. At this time the connection is again established between the calling subscriber substation T1 and the called subscriber substation in the distant exchange B.

Also, the operator at the first operator position 1400 may wish to split the connection routed by way of the finder-selector link illustrated and talk to the called party to the exclusion of the calling party. This is accomplished by operating the talk key 780 of the finder switch 700 to its operated position as previously explained. The operator at the first operator position then operates the cut-off key K6 to its front position, thereby to complete, at the contact 1440 thereof, a circuit for energizing the rear split relay R1220, the last-mentioned circuit extending from ground at the contact 1440 of the cut-off key K6 by way of the conductor C1465 and the winding of R1220 to battery. When energized over the above-traced circuit, the rear split relay R1220 operates, as previously explained, to disconnect, at RA1221 and RC1222 and at RA1224 and RC1225, the conductors C1276 and C1275 included in the cable 1286 from the trunk circuit at the first operator position. At this time the conductors C1275 and C1276 included in the cable 1286 and connected by way of the finder switch 700 to the trunk line 460 are disconnected from the trunk circuit at the first operator position; and the conductors C1277 and C1278 included in the cable 1286 and connected to the line conductors of the trunk line 793 extending to the toll selector switch 800 are connected to the trunk circuit at the first operator position. Accordingly, the operator at the first operator position 1400 may converse with the called subscriber in the distant exchange B to the exclusion of the calling subscriber at the substation T1. After the operator at the first operator position 1400 has finished her conversation with the called party in the distant exchange B, the cut-off key K6 is returned to its normal position, thereby to interrupt, at the contact 1440 thereof, the previously traced circuit for energizing the rear split relay R1220, whereupon the latter relay, being of the slow-to-release type, restores shortly thereafter to reconnect the conductors C1275 and C1276 in the cable 1286 to the trunk circuit at the first operator position.

It is noted that, in the event an operator at any position at the toll board finds it necessary to vacate her position at a time when a call is routed by way of one of the finder-selector links individually associated with her position, she may

transfer the call to the succeeding operator position for supervision. For example, in the event that the operator at the first operator position 1400 desires to vacate her position during the time when the established connection is routed by way of the finder-selector link illustrated, she may transfer the call to the succeeding operator for supervision by operating the transfer key K9 at her position. When the transfer key K9 is operated, an obvious circuit is completed, at the contact 1410 thereof, for energizing the transfer relay R1200, thereby to cause the latter relay to operate. Upon operating, the transfer relay R1200 completes, at RA1201 and RC1202, a connection between the conductor C1280 in the cable 1286 connected to the line conductor C1180 of the trunk circuit at the first operator position and the conductor C1280' extending to the succeeding operator position and completes, at RA1203 and RC1204, a connection between the conductor C1281 in the cable 1286 connected to the line conductor C1181 of the trunk circuit at the first operator position and the conductor C1281' extending to the succeeding operator position. Also, at RA1205 and RC1205, the conductor C1282 in the cable 1286 is connected to the conductor C1282' extending to the succeeding operator position; at RA1207 and RC1208, the conductor C1283 in the cable 1286 is connected to the conductor C1283' extending to the succeeding operator position; and, at RA1209 and RC1209, the conductor C1285 in the cable 1286 is connected to the conductor C1285' extending to the succeeding operator position.

At this time, in the event the monitor key 770 of the finder switch 700 is operated away from its normal position, the connection between the conductors C1280, C1281 and C1282 in the cable 1286 and the conductors C1280', C1281' and C1282', respectively, extending to the succeeding operator position renders the succeeding operator position operative to monitor the established connection routed by way of the finder-selector link illustrated. Also, at this time, in the event the talk key 780 of the finder switch 700 is operated away from its normal position, the connection between the line conductors C1180 and C1181 of the trunk circuit at the first operator position and the conductors C1280' and C1281', respectively, extending to the succeeding operator position, and the connection between the conductors C1283 and C1285 in the cable 1286 and the conductors C1283' and C1285' extending to the succeeding operator position renders the succeeding operator position operative to communicate over the established connection routed by way of the finder-selector link illustrated.

When the operator returns to the first operator position 1400, she operates the transfer key K9 back to its normal position, thereby to interrupt the previously mentioned circuit for energizing the transfer relay R1200 in order to cause the latter relay to restore. Upon restoring, the transfer relay R1200 interrupts the previously traced connections between the conductors mentioned in the cable 1286 and the trunk circuit at the first operator position and the conductors mentioned extending to the succeeding operator position, thereby to render the supervision of the established connection routed by way of the finder-selector link illustrated under the control of the operator at the first operator position.

Release of an established connection at the switchboard

An established connection routed by way of one of the finder-selector links individually associated with one of the operator positions is primarily under the control of the operator thereat. For example, the release of the established connection routed by way of the finder-selector link illustrated is primarily under the control of the operator at the first operator position 1400. However, disconnect supervision is provided at the first operator position 1400 in order to indicate to the operator thereat when the subscriber at either end of the connection has replaced the receiver of the telephone instrument at his substation upon its hook, as previously noted. When the subscriber at the calling substation T1 replaces the receiver of the telephone instrument upon its hook, the relay R440 in the C. L. R. trunk circuit 400 restores, thereby to complete, at RA441 and RC442, one or the other of the previously traced circuits for illuminating the supervisory lamp L767. The supervisory lamp L767 is illuminated directly from ground, at RA441 of the relay R440 in the C. L. R. trunk circuit 400, by way of the previously traced circuit, in the event the talk key 780 of the finder switch 700 is restored to its normal position, when the subscriber at the calling subscriber substation T1 replaces the receiver of the telephone instrument thereat upon its hook, as previously explained. Also, the previously traced circuit for illuminating the supervisory lamp L767 is completed from ground, at RA1231 of the supervisory relay R1230 in the relay group 1200A, in the event the talk key 780 is operated away from its normal position, when the subscriber at the calling substation T1 replaces the receiver of the telephone instrument thereat upon its hook, as previously explained.

When the subscriber at the called substation in the distant exchange B replaces the receiver of the telephone instrument thereat upon its hook, the operator at the toll operator position in the distant exchange B is given a disconnect signal, whereupon this operator causes a disconnect signal to be transmitted over the toll line 340. When the disconnect signal is transmitted over the toll line 340, the ring-down toll line circuit 310, individually associated therewith, operates to cause ground potential to be applied to the control conductor of the trunk line 320 terminated in the main contact bank of the mechanism 801 of the toll selector switch 800 engaged by the wiper 804 of the wiper set of this mechanism. One of two alternative circuits is completed for illuminating the supervisory lamp L776 at this time, depending upon the position of the talk key 780 of the finder switch 700. In the event the talk key 780 is restored to its normal position, the circuit for illuminating the supervisory lamp L776 extends from the grounded wiper 804 of the wiper set of the mechanism 801 by way of RA871, the conductor C789 of the trunk line 793, RA763, the supervisory lamp L776 and the contact 775 of the talk key 780 to battery. On the other hand, in the event the talk key 780 is operated away from its normal position at this time, a circuit is first completed for energizing the relay R1120 in the relay group 1200A, this circuit extending from the grounded wiper 804 of the wiper set of the mechanism 801 by way of RA871, C789, RA763, the supervisory lamp L776, the contact 774 of the talk key 780, 75

the conductor C1284 in the cable 1286, RA1217, RC1219, C1185, the resistor 1122 and the winding of R1120 to battery. When energized over the above-traced circuit, the relay R1120 operates to complete, at RA1121, an obvious path for short-circuiting the resistor 1122, thereby to reduce the series resistance of the above-traced circuit. When the series resistance of the above-traced circuit is thus reduced, the supervisory lamp L176 circuit is thus reduced, the supervisory lamp L176 0 is illuminated.

The illumination of the supervisory lamp L176 indicates to the operator at the first operator position 1400 that the calling party at the substation T1 desires attention or has replaced the receiver of the telephone instrument thereat upon its hook. Likewise, the illumination of the supervisory lamp L176 indicates to the operator at the first operator position that the called party in the distant exchange B desires attention or has 15 replaced the receiver of the telephone instrument at his substation upon its hook.

The operator at the first operator position 1400 then operates the talk key 780 away from its normal position, in the event that it occupies its 20 restored position at this time, and listens in upon the established connection, thereby to ascertain whether the calling or called party desires attention or has replaced the receiver of the telephone instrument at his substation upon 25 its hook.

The operator at the first operator position may release the front end of the established connection or the rear end thereof selectively, as she desires, or she may release both ends of the established connection simultaneously. The manner in which the release of the established connection is effected depends upon whether the operator at the first operator position 1400 desires to communicate with either the calling or the called 30 party subsequently. Moreover, the operator at the first operator position may release the front end of the established connection while the calling party at the rear end of the established connection retains his connection to the first operator 35 position and then subsequently extend the front end of the connection to another destination in the event the calling party so desires.

In order to release the rear end of the established connection without releasing the front end thereof, the operator at the first operator position 1400 operates the release key K8 to its rear position, the talk key 780 of the finder switch 700 being operated away from its normal position at this time. When the release key K8 is operated 40 to its rear position, a circuit is completed, at the contact 1436 thereof, for energizing the winding of the rear split relay R1220, this circuit extending from ground at the contact 1436 by way of C1465 and the winding of R1220 to battery. When energized over the above-traced circuit, the rear-split relay R1220 operates, as previously 45 explained, thereby to disconnect the conductors C1275 and C1276 included in the cable 1286 from the trunk circuit at the first operator position. The conductors mentioned included in the cable 1286 are disconnected from the trunk circuit at the first operator position in order to prevent disagreeable clicks from being transmitted to the 50 trunk circuit at the first operator position incident to the release of the local switch train, as described hereinafter.

Also, when the release key K8 is operated to its rear position, an obvious path is completed, at the contact 1437 thereof, for applying ground 55 potential to the release conductor C1461 included

in the cable 1286. This application of ground potential to the release conductor C1461 included in the cable 1286 completes a path for short-circuiting the upper winding of the switch-over relay R720 in the finder switch 700, this path extending from the grounded release conductor C1461 by way of RA1757, the sets of switch springs S1783 and S1784, and the winding of R720 to ground. Also, this application of ground potential to the release conductor C1461 completes an obvious path for short-circuiting the answer pilot relay R1260 in the relay group 1200A. When the relays R720 and R1260 are thus short-circuited they restore. Upon restoring, the answer pilot relay R1260 interrupts, at RA1261 15 and RC1263, a point in the previously traced circuit for energizing the start relay R740, thereby to cause the latter relay to restore. Upon restoring, the start relay R740 interrupts, at RA1742, a point in the previously mentioned circuit for energizing the upper winding of the electropolarized relay R710 and prepares, at RA1747, a further point in the previously mentioned circuit for energizing the release magnet M735 of the mechanism 701 in the finder switch 700. Upon restoring, the switch-over relay R720 interrupts, at RA1726 and RC1727, a point in the previously traced holding circuit for energizing the lower winding of the electropolarized relay R710, thereby to cause the latter relay to restore, 20 and completes, at RA1726 and RC1728, a point in the previously mentioned circuit for energizing the release magnet M735. The last-mentioned circuit extends from ground at RA1726 by way of RC1728, RA1747, the set of switch springs S1785 25 and the winding of M735 to battery. When the release magnet M735 is energized over the above-traced circuit, it operates to release the wiper set of the mechanism 701 and to cause the wiper set thereof to be returned to its normal position. 30 Also, upon restoring, the switch-over relay R720 interrupts, at RA1726 and RC1727, a point in the previously traced circuit for energizing the relay R420 in the C. L. R. trunk circuit 400, thereby to cause the latter relay to restore. Upon restoring, 35 the relay R420 interrupts, at RA421, a point in the previously mentioned alternative circuit for energizing the winding of the relay R430 and interrupts, at RA422 and RC423, a point in the previously mentioned path for applying ground 40 potential to the control conductor C451 of the C. L. R. trunk 450.

Assuming, at this time, that the calling subscriber at the substation T1 has replaced the receiver of the telephone instrument thereat upon its hook, the relay R440 occupies its restored position. Accordingly, the previously mentioned original circuit for energizing the winding of the relay R430 is interrupted at RA441 and RC443. Hence, the relay R430 restores, at this time, to interrupt, at RA431, a further point in the previously traced circuit for energizing the relay R420 and interrupts, at RA432, a point in the original circuit for applying ground potential to the control conductor C451 55 of the C. L. R. trunk 450. When ground potential is removed from the control conductor C451 of the C. L. R. trunk 450, the local switch trains including the selector switch 472 and the finder switch 471 restore to their normal positions. 60 Also, when the local switch train is released, the line circuit 961 individually associated with the subscriber line 962 operates, thereby to mark the subscriber line 962 as idle. At this time the local 65 switch train and the C. L. R. trunk circuit 400 70 switch train 75

are completely released for further use. However, the front end of the connection has not been released. Accordingly, the toll selector switch 800 remains in its operated position.

- 5 It is noted that, at this time, the call pilot relay R1320 in the relay group 1200A remains in its operated position, thereby to interrupt, at RA1321, a point in the previously traced circuit for energizing the distributor start relay R1310 10 in order to prevent an incoming call from being routed into the first operator position 1400 at this time. Also, the operated call pilot relay R1320 interrupts, at RA1322, a further point in the previously traced path for applying ground 15 potential to the start conductor C1360 included in the cable 1367 extending to the sender control circuit 300, thereby to prevent operation of the sender control circuit 300 at this time.

In order to release the front end of the established connection without releasing the rear end thereof, the operator at the first operator position 1400 operates the release key K8 to its front position. When the release key K8 is operated to its front position, a circuit is completed, at 20 the contact 1438 thereof, for energizing the front split relay R1210, this circuit extending from ground at the contact 1438 by way of C1467 and the winding of R1210 to battery. When energized over the above-traced circuit, the front 25 split relay R1210 operates to disconnect, at RA1211 and RC1212 and at RA1214 and RC1215, the conductors C1278 and C1277 included in the cable 1286 from the trunk circuit at the first operator position, thereby to eliminate disagreeable 30 clicks from being transmitted to the trunk circuit at the first operator position incident to the release of the toll switch train.

Also, at the contact 1439 of the release key K8, an obvious path is completed for applying ground 35 potential to the release conductor C1460 included in the cable 1286. This application of ground potential to the release conductor C1460 completes a path for short-circuiting the lower winding of the cut-through relay R760, this path extending from the grounded release conductor C1460 by way of RA751', RA765 and the lower winding of R760 to ground. When the lower winding of the cut-through relay R760 is thus short-circuited, this relay restores to interrupt, 40 at RA765, a further point in the holding circuit for energizing the lower winding thereof and to interrupt, at RA764, a point in the previously mentioned path for applying ground potential to the control conductor C790 of the trunk line 50 55 793 extending to the toll selector switch 800. Also, upon restoring, the cut-through relay R760 interrupts, at RA761, RA762 and RA763, the connection between the finder switch 700 and the trunk line 793 extending to the toll selector switch 800.

When ground potential is removed from the control conductor C790 of the trunk line 793, the previously traced holding circuit for energizing the intermediate winding of the electropolarized relay R810 in the toll selector switch 800 is interrupted, thereby to cause the latter relay to restore and interrupt, at RA816, a further point in the previously traced holding circuit for energizing the intermediate winding thereof. Also, 60 upon restoring, the electropolarized relay R810 completes, at RA818, the previously mentioned circuit for energizing the release magnet M805 of the mechanism 801, this circuit extending from ground at RA818 by way of RA822, RC824, 65 RA834, RC836, the set of switch springs S888 and

the winding of M805 to battery. When energized over the above-traced circuit, the release magnet M805 operates to release the wiper set of the mechanism 801 and to cause this wiper set to be returned to its normal position. Also, upon restoring, the electropolarized relay R810 interrupts, at RA811 and RC812 and at RA813 and RC814, further points in the previously traced connection between the line conductors of the trunk line 793 extending to the toll selector switch 800 and the wiper set of the mechanism 801 and prepares, at RA811 and RC811 and at RA813 and RC813, points in the previously traced circuit for energizing the upper and lower windings of the line relay R820. Moreover, the electropolarized relay R810 interrupts, at RA815, a point in the previously traced path for applying ground potential to the wiper 805 of the wiper set of the mechanism 801 for a purpose more fully explained subsequently. At this time the toll selector switch 800 is completely released for further use.

When ground potential is removed from the wiper 805 of the wiper set of the mechanism 801, the previously mentioned path for applying ground potential to the control conductor of the trunk line 320 extending to the ring-down toll line circuit 310 is interrupted, thereby to cause the ring-down toll line circuit 310 to operate and mark the toll line 340 as idle to the switches 30 having access thereto. The toll operator in the distant exchange B releases the connection to the called subscriber therein in the usual manner.

After the operator at the first operator position 1400 operates the release key K8 to its front position, as previously explained, in order to cause the front end of the connection to be released, she returns this key to its normal position, thereby to interrupt, at the contact 1438 thereof, a point in the previously traced circuit for energizing the front split relay R1210. Shortly thereafter, the front split relay R1210 restores to reconnect, at RA1211 and RC1212 and at RA1214 and RC1215, the conductors C1278 and C1277 included in the cable 1286 to the line conductors C1180 and C1181, respectively, of the trunk circuit at the first operator position. Also, when the release key K8 is returned to its normal position, a point is interrupted, at the contact 1439 thereof, in the previously mentioned path for applying ground potential to the release conductor C1460, thereby to interrupt the previously traced circuit for energizing the call pilot relay R1320, thus causing the latter relay to restore shortly thereafter, the latter relay being of the slow-to-release type. Upon restoring, the call pilot relay R1320 completes, at RA1322, a point in the previously traced circuit for applying ground potential to the start conductor C1360 included in the cable 1367 extending to the sender control circuit 300. This application of ground potential to the start conductor C1360 causes the sender control circuit 300 to operate in the previously described manner, thereby to associate an idle digit register and control circuit therewith and to find the cable 786 individually extending to the finder-selector link illustrated. At this time the finder switch 700 is operatively connected with the calling subscriber substation T1, and when the sender control circuit 300 operates to find the cable 786 individually extending to the finder-selector link illustrated, the line relay R820 in the toll selector switch 800 operates in the previously described manner, thereby to condition the toll selector switch 800 to be 70 75

responsive to impulses transmitted thereto from the sender control circuit 300. At this time the operator at the first operator position 1400 may extend the connection from her position to any 5 desired destination, in the previously described manner, by again operating the sending key set 303 at her position.

As previously noted, the operator at the first operator position 1400 may release simultaneously 10 both the front and the rear ends of an established connection routed by way of one of the finder-selector links individually associated with her position. For example, in order to release simultaneously both ends of the established connection 15 routed by way of the finder-selector link illustrated, the operator at the first operator position operates the release and start key K7 to its left-hand position. When the release and start key K7 is operated to its left-hand position, obvious 20 circuits are completed, at the contacts 1430 and 1431 thereof, for energizing the windings of the front split and the rear split relays R1210 and R1220, respectively, thereby to cause the latter relays to operate. Upon operating, the front split 25 relay R1210 disconnects the conductors C1277 and C1278 from the trunk circuit at the first operator position; and, upon operating, the rear split relay R1220 disconnects the conductors C1275 and C1276 from the trunk circuit at the first operator 30 position, thereby to prevent disagreeable clicks from being transmitted to the trunk circuit at the first operator position incident to the release of the rear and forward switch trains, respectively, as previously explained. Also, when the release 35 and start key K7 is operated to its left-hand position, obvious paths are completed, at the contacts C1432 and C1433 thereof, for applying ground potential to the release conductors C1460 and C1461, respectively. The application 40 of ground potential to the release conductor C1460 causes the forward end of the connection to be released as previously explained; and the application of ground potential to the release conductor C1461 causes the rear end of the connection 45 to be released in the manner previously explained. After operating the release and start key K7 to its left-hand position, the operator at the first operator position returns this key to its normal position, thereby to condition the first 50 operator position to receive another call incoming to the toll board. At this time the toll selector switch 800 is completely released and the start and connect relays R740 and R750, respectively, in the finder switch 700 occupy their operated 55 positions, the talk key 780 being operated at this time, thereby to condition the finder switch 700 to operate when the next incoming call to the switchboard is routed thereto by the common start and position distributor apparatus 330.

60 Also, at this time, the talk relay R1130 in the relay group 1200A at the first operator position occupies its operated position as previously explained, thereby to complete, at RA1137 and 65 RC1138, the previously traced circuit for energizing the distributor start relay R1310, additional points in the last-mentioned circuit being prepared, at RA1266 and RA1321, incident to the restoration of the answer pilot relay R1260 and 70 the call pilot relay R1320, respectively. When thus energized, the distributor start relay R1310 operates, as previously explained, thereby to mark the first operator position 1400 as idle and in readiness to receive an incoming call to the 75 switchboard routed thereto by the common start

and position distributor apparatus 330. The subsequent operation of the common start and position distributor apparatus 330 to route an incoming call to the switchboard to the first operator position 1400 to be answered is the same as that 5 previously explained.

Extension of a call from a paystation in the central office A to the switchboard

Calls initiated at the paystations in the central office A are answered at the switchboard and routed therefrom to their destinations. For example, in order to initiate a call at the paystation T2, the calling party removes the receiver of the telephone instrument thereat from its hook 10 and places a coin in the coin slot of the instrument. When the coin is placed in the coin slot of the instrument at the paystation T2, a path is completed at the paystation T2 for applying ground potential by way of the conductor C1504 15 to the line conductors C1502 and C1503 of the paystation line 1501. This application of ground potential to the line conductors C1502 and C1503 of the paystation line 1501 completes multiple circuits for energizing the upper winding of the 20 relay R1520 in the paystation line circuit 1500. One of these circuits extends from the grounded line conductor C1502 by way of RA1541, RC1542 and the upper winding of R1520 to battery; and the other of these circuits extends from the 25 grounded line conductor C1503 by way of RA1545, RC1547, RA1537, RC1539 and the upper winding of R1520 to battery. When energized over the 30 above-traced circuits, the relay R1520 operates to complete, at RA1522, a holding circuit for energizing the upper and lower windings thereof in series, due to the fact that the ground potential applied to the line conductors C1502 and C1503 of the paystation line 1501 is only momentarily applied thereto. The last-mentioned circuit 35 extends from ground at the lower winding of R1520 by way of the lower winding of R1520, RA1532, the resistor 1529, RA1522 and the upper winding of R1520 to battery. Also, upon operating, the relay R1520 interrupts, at RA1523 and RC1525, 40 a point in a circuit, traced hereinafter, for energizing the lower winding of the relay R1540 and completes, at RA1523 and RC1524, an obvious path for applying ground potential to the control conductor C1512 of the trunk line 1510, thereby 45 to mark the paystation line circuit 1500 as busy to the switches having access thereto. Also, the relay R1520 completes, at RA1521, an obvious path for applying battery potential, at the winding of the relay R1530, to the control conductor 50 C1516 of the trunk line 1514 extending to the finder switches of the finder-selector links associated with the operator positions at the switchboard. Finally, the relay 1520 completes, at RA1526 and RC1527, a point in a path for applying ground 55 potential to the start conductor C1550 extending to the common start and position distributor apparatus 330, the last-mentioned path extending from ground at RA1526 by way of RC1527 and RA1536 to the start conductor C1550. 60

This application of ground potential to the start conductor C1550 causes the common start and position distributor apparatus 330 to operate and route the call to one of the operator positions at the switchboard to be answered, as previously explained. Assuming that the operator at the first operator position 1400 is awaiting a call and has operated the talk key 780 of the finder switch 700 of the finder-selector link illustrated away from its normal position, thereby 75

to condition the finder switch 700 to be operative to find a trunk line having a calling condition thereon and that the common start and position distributor apparatus 330 operates and selects the 5 first operator position as the position to which the incoming call to the switchboard is to be routed, the common start and position distributor apparatus 330 then operates to cause ground potential to be applied to the start conductor C1372 10 included in the cable 1374 extending to the first operator position as previously explained. This application of ground potential to the start conductor C1372 completes the previously traced path for applying ground potential to the conductor C1287 included in the cable 1286, thereby to complete the previously traced circuit for energizing the start relay R140 in the finder switch 700. When the start relay R140 is thus energized, the finder switch 700 operates to find the 15 trunk line having the calling condition thereon in the previously described manner. At this time the trunk line 1514 terminated in the main contact bank of the mechanism 701 included in the finder switch 700 and extending to the pay-sta- 20 tion line circuit 1500 has a calling condition thereon, as previously explained. Accordingly, the finder switch 700 operates to seize the trunk line 1514.

As previously noted, the common start and position distributor apparatus 330 operates to mark, by way of the cable 785 in the vertical control bank 109 of the mechanism 701, the vertical level wherein the trunk line 1514 is terminated. Also, the rotary position wherein the trunk line 35 1514 is terminated is marked by the presence of battery potential appearing upon the control conductor C1516 of the trunk line 1514, the wiper 707 of the wiper set of the mechanism 701 engaging the contact in the main contact bank terminating the control conductor C1516 of the 40 trunk line 1514 at this time.

Also, as previously noted, the common start and position distributor apparatus 330 operates to cause ground potential to be applied to the 45 control conductor C1461 in the cable 1374 extending to the first operator position 1400, thereby to complete the previously traced circuit for illuminating the trunk answer lamp L1463. The illumination of the trunk answer lamp L1463 in- 50 dicates to the operator at the first operator position that the incoming call which has been extended thereto is a trunk call. More specifically, the trunk answer lamps at the first operator position are so connected and arranged that the 55 illumination of the trunk answer lamp L1463 indicates to the operator at the first operator position 1400 that the incoming trunk call is from a paystation.

As previously noted, when the finder switch 700 60 operates to seize the trunk line 1514, the electro-polarized relay R710 therein operates to complete, at RA718, an obvious path for short-circuiting the intermediate winding thereof, thereby to reduce the series resistance of a circuit, 65 traced hereinafter, for energizing the winding of the relay R1530 in the paystation line circuit 1500. The last-mentioned circuit extends from ground at RA126 by way of RC127, RA118, the wiper 707 of the wiper set of the mechanism 701, 70 the control conductor C1516 of the trunk line 1514, RA1521, and the winding of R1530 to battery. When energized over the above-traced circuit, the relay R1530 operates to complete, at RA1531, an obvious holding circuit for energizing 75 the winding thereof by way of the grounded con-

trol conductor C1516 of the trunk line 1514. Also, upon operating, the relay R1530 interrupts, at RA1532, a point in the previously traced holding circuit for energizing in series the upper and lower windings of the relay R1520 and completes, 5 at RA1533 and RC1538, an alternative holding circuit for energizing in series the upper and lower windings of the relay R1520. The last-mentioned circuit extends from ground at the lower winding of R1520, by way of the lower winding of R1520, RC1538, RA1531, RC1541, RA1545 and the line conductor C1513 of the trunk line 1510 to the line conductor C1503 of the paystation line 1501, and from battery at the upper winding of R1520, by way of the upper winding of 15 R1520, RC1542, RA1541 and the line conductor C1511 of the trunk line 1510 to the line conductor C1502 of the paystation line 1501, the line conductors C1503 and C1502 of the paystation line 1501 being connected together by way of the 20 switchhook and telephone instrument at the paystation T2. Also, the relay R1530 prepares, at RA1534 and RC1533, a point in a path, traced hereinafter, for applying ground potential to the control conductor C1512 of the trunk line 1510 25 and interrupts, at RA1536, a point in the previously traced path for applying ground potential to the start conductor C1550 extending to the common start and position distributor apparatus 330. At this time talking battery is supplied 30 from the relay R1520 in the paystation line circuit 1500 to the telephone instrument at the paystation T2 and the line conductors C1511 and C1513 of the trunk line 1510 are capacitively coupled to the line conductors C1515 and C1519, re- 35 spectively, of the trunk line 1514 by the condensers 1548 and 1549, respectively. When ground potential is removed from the start conductor C1550 extending to the common start and position distributor apparatus 330, further operation 40 of the last-mentioned apparatus is arrested, as previously explained.

The operator at the first operator position 1400 then answers the call and communicates with the subscriber at the paystation T2 in order to 45 ascertain the destination to which the call is to be extended. The operator at the first operator position, after learning the destination of the call, operates the sending key set 303 at her position in the previously described manner, thereby 50 to cause the toll selector switch 800 to operate and extend the call to its destination as previously explained.

After a connection has been established from the first operator position 1400 by way of the 55 toll selector switch 800 to the called subscriber substation in the previously described manner, the operator operates the coin collect key K2, thereby to cause the apparatus at the paystation T2 to operate and collect the coin which has been 60 inserted in the coin slot of the instrument therewith. More particularly, the operator at the first operator position 1400 operates the coin collect key K2 to its rear position, whereupon a circuit is completed, at the contact 1421 thereof, for energizing the rear split relay R1220, the last-mentioned circuit extending from ground at the contact 1421 by way of C1465 and the winding of R1220 to battery. When energized over the above-traced circuit, the rear split relay R1220 65 operates to disconnect, at RA1221 and RC1222 and at RA1224 and RC1225, the conductors C1276 and C1275, respectively, from the line conductors C1180 and C1181 of the trunk circuit at the first operator position and to connect the 70 75

- conductors C1276 and C1275, at RA1221 and RC1223 and at RA1224 and RC1226, to the line conductors C1366 and C1365, respectively, of the trunk circuit at the first operator position. The 5 disconnection of the conductors C1275 and C1276 included in the cable 1286 from the line conductors C1280 and C1281 of the trunk circuit at the first operator position prevents disagreeable clicks in the receiver of the telephone instrument.
- 10 10 connection of the conductors C1275 and C1276 included in the cable 1286 from the line conductors C1280 and C1281 of the trunk circuit at the first operator position prevents disagreeable clicks in the receiver of the telephone instrument thereat incident to the projection of current over the trunk line 1514 in order to control coin collection at the paystation T2. Also, when the coin collect key K2 is operated to its rear position, a circuit is completed, at the contact 15 1423 thereof, for energizing in series the rear coin control relay R1250 in the relay group 1200A and the upper winding of the relay R1540 in the paystation line circuit 1500. The last-mentioned circuit extends from ground at the contact 1423 by way of C1462, the winding of R1250, the conductor C1380 in the cable 1286, RA741, RA713, the wiper 704 of the wiper set of the mechanism 701 of the finder switch 700, the control conductor C1517 of the trunk line 1514, and the upper 20 winding of R1540 to battery. When energized over the above-traced circuit, the rear coin control relay R1250 operates to complete, at RA1251 and RC1253, an obvious path for connecting together the line conductors C1366 and C1365 of the trunk circuit at the first operator position.
- 25 30 When the relay R1540 in the paystation line circuit 1500 is thus energized, the latter relay operates to complete, at RA1544, an alternative holding circuit for energizing the winding of the relay R1530. The last-mentioned circuit extends from ground at RA1544 by way of the control conductor C1516 of the trunk line 1514, RA1531 and the winding of R1530 to battery. Also upon operating, the relay R1540 completes, at RA1541 and RC1543, an obvious path for short-circuiting the condenser 1548 included in the line conductor C1515 of the trunk line 1514 and completes, at RA1545 and RC1546, an obvious path for short-circuiting the condenser 1549 included in the line conductor C1519 of the trunk line 1514. Prior to the operation of the relay R1540, the line conductors C1502 and C1503 of the paystation line 1501 were capacitively coupled to the line conductors C1515 and C1519, respectively, of the 35 40 45 trunk line 1514. However, after operation of the relay R1540, the line conductors C1502 and C1503 of the paystation line 1501 are metallically connected to the line conductors C1515 and C1519, respectively, of the trunk line 1514.
- 50 55 Moreover, when the coin collect key K2 is operated to its rear position, an obvious path is completed, at the contact 1424 thereof, for connecting the positive terminal of a 110 volt D. C. source of supply to the conductor C1463. This 60 application of positive potential to the conductor C1463 completes a circuit for projecting current over the line conductors C1515 and C1519 of the trunk line 1514 in parallel circuit relationship to the paystation T2, due to the fact that the conductor C1463 is directly connected to the line conductor C1365 of the trunk circuit at the first operator position; while the line conductors C1365 and C1366 of the trunk circuit at the first operator position 1400 are connected together and 65 to the conductors C1275 and C1276 in the cable 1286. The last-mentioned conductors in the cable 1286 are connected by way of the finder switch 700 to the line conductors C1515 and C1519 of the trunk line 1514; and the last-mentioned line 70 75 conductors of the trunk line 1514 are connected to the line conductors C1502 and C1503 of the paystation line 1501. When current is thus projected over the line conductors of the paystation line 1501, apparatus in the paystation T2 operates, thereby to cause the coin inserted in the 5 coin slot of the instrument thereat to be collected.
- 80 85 After operating the coin collect key K2 to its rear position, thereby to collect the coin at the paystation T2, the operator at the first operator position returns this key to its normal position. When the coin collect key K2 is returned to its normal position, the previously traced circuit for energizing the rear split relay R1220 is interrupted, at the contact 1421 thereof, thereby to 15 cause the rear split relay R1220 to restore shortly thereafter. Also, the previously traced circuit for energizing in series the rear coin control relay R1250 in the relay group 1200A and the relay R1240 in the paystation line circuit 1500 is interrupted at the contact 1423 of the coin collect key K2. Finally, at the contact 1424 of the coin collect key K2, the previously traced path for applying positive potential to the conductor C1463 is interrupted. When the previously traced circuit for energizing in series the relays R1250 and R1240 is interrupted, the relay R1250 restores immediately, while the relay R1540 restores shortly thereafter, the latter relay being of the slow-to-release type.
- 90 95 Upon restoring, the rear coin control relay R1250 interrupts, at RA1251 and RC1253, the previously mentioned connection between the line conductors C1365 and C1366 of the trunk circuit at the first operator position. When the rear split relay R1220 restores, the conductors C1275 and C1276 are disconnected from the line conductors C1365 and C1366 and again connected to the line conductors C1181 and C1180 of the trunk circuit at the first operator position. At this time the telephone instrument at the first operator position is again operatively connected with the trunk line 1514 extending to the paystation line 1500.
- 100 105 Upon restoring, the relay R1540 in the paystation line circuit 1500 interrupts, at RA1544, the previously traced alternative holding circuit for energizing the winding of the relay R1530. However, the latter relay remains in its operated condition due to the completed holding circuit 50 for energizing the winding thereof including the control conductor C1516 of the trunk line 1514. Also, upon restoring, the relay R1540 interrupts, at RA1541 and RC1543 and at RA1545 and RC1546, points in the previously traced paths 55 for short-circuiting the condensers 1548 and 1549, respectively. At this time the line conductors C1515 and C1519 of the trunk line 1514 are capacitively coupled to the line conductors C1502 and C1503, respectively, of the paystation line 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 is operated, the previously traced circuit for energizing in series the upper and lower windings of the relay R1520 is interrupted, thereby to cause the latter relay to restore. Conversely, each time the switchhook at the paystation T2 is released, the previously traced circuit for energizing in series the upper and lower windings of the relay R1520 is recompleted, thereby to cause the latter relay to reoperate. Each time the relay R1520 restores it completes, at RA1523 and RC1525, an alternative path for applying ground potential to the control conductor C1512 of the trunk line 1510, this path extending from ground at RC1533 by way of RA1534, RC1525 and RA1523 to the control conductor C1512. This application of ground potential to the control conductor C1512 of the trunk line 1510 marks the paystation line circuit 1500 as busy to the switches having access thereto, as previously explained. Also, upon restoring, the relay R1520 completes, at RA1526 and RC1528, an obvious path for applying ground potential to the control conductor C1518 of the trunk line 1514. This application of ground potential to the control conductor C1518 of the trunk line 1514 causes the supervisory lamp L767 to be illuminated regardless of the position of the talk key 780 of the finder switch 700. In the event the talk key 780 of the finder switch 700 occupies its normal position, this application of ground potential to the control conductor C1518 of the trunk line 1514 completes a circuit for illuminating the supervisory lamp L767, this circuit extending from the grounded control conductor C1518 of the trunk line 1514 by way of the wiper 706 of the wiper set of the mechanism 701 in the finder switch 700, RA1717, RA1744, RC745 and the supervisory lamp L767 to battery. On the other hand, in the event the talk key 780 of the finder switch 700 is operated away from its normal position at this time, this application of ground potential to the control conductor C1518 of the trunk line 1514 completes a circuit for energizing the supervisory relay R1230 in the relay group 1200A, this circuit extending from the grounded control conductor C1518 of the trunk line 1514 by way of the wiper 706 of the wiper set of the mechanism 701 of the finder switch 700, RA1717, RA1744, RA1743, the conductor C1383 in the cable 1286, RA1346, RC1348, C1384, RA1227, RC1229, the resistor 1232 and the winding of R1230 to battery. When energized over the above-traced circuit, the supervisory relay R1230 operates to complete, at RA1231, a circuit for illuminating the supervisory lamp L767, this circuit extending from ground at RA1231 by way of the conductor C1274 in the cable 1286, RA1746 and the supervisory lamp L767 to battery. Accordingly, intermittent operation of the switchhook at the paystation T2 by the calling party thereto causes the supervisory lamp L767 to flash, thereby to indicate to the operator at the first operator position 1400 that the calling party at the paystation T2 desires her attention.

The supervision of the established connection including the calling paystation T2 is under the control of the operator at the first operator position 1400 and is accomplished in the manner previously explained.

In the event the operator at the first operator position 1400 is unable to extend the call at her position to the desired destination, the subscriber at the paystation T2 is so informed and the coin which he has inserted in the coin slot of the instrument thereat is refunded to him. This is accomplished by the operator at the first operator

position upon operating the coin return key K1 to its rear position. When the coin return key K1 is operated to its rear position, a circuit is completed, at the contact 1414 thereof, for energizing the winding of the rear split relay R1220, this circuit extending from ground at the contact 1414 by way of C1465 and the winding of R1220 to battery. When the rear split relay R1220 is thus energized, it operates as previously explained. Also, at the contact 1418 of the coin return key K1, an obvious path is completed for applying ground potential to the conductor C1462, thereby to complete the previously traced circuit for energizing in series the rear coin control relay R1250 in the relay group 1200A and the relay R1540 in the paystation line circuit 1500. When the relays R1250 and R1540 are thus energized, they operate as previously explained. Finally, at the contact 1417 of the coin return key K1, an obvious path is completed for connecting the negative terminal of a 110 volt D. C. source of supply to the conductors C1463, thereby to complete the previously traced path for projecting current over the line conductors C1515 and C1519 of the trunk line 1514 in parallel to the paystation T2 as previously explained. When current is thus projected to the paystation T2, apparatus thereat operates in order to cause the coin which the calling subscriber has placed in the coin slot of the instrument thereat to be returned to him.

After operating the coin return key K1 to its rear position, the operator at the first operator position 1400 returns this key to its normal position, thereby to interrupt, at the contact 1414 thereof, the previously traced circuit for energizing the rear split relay R1220, to interrupt at the contact 1416 thereof, the previously traced circuit for energizing in series the rear coin control relay R1250 and the relay R1540, and to interrupt, at the contact 1417 thereof, the previously traced path for connecting the negative terminal of a 110 volt D. C. source of supply to the conductor C1463. When the circuits for energizing the front split relay R1210, the rear coin control relay R1250 and the relay R1540 are thus interrupted, these relays restore, as previously explained. At this time the telephone instrument at the first operator position 1400 is operatively connected with the telephone instrument at the paystation T2 for further communication, if desired.

The release of the connection between the paystation T2 and the switchboard, and the release of an established connection including the paystation T2 and routed by way of the finder-selector link illustrated, is under the control of the operator at the first operator position 1400 and is accomplished in the previously described manner.

It is noted that when the finder switch 700 of the finder-selector link illustrated is returned to its normal position, ground potential is removed from the control conductor C1518 of the trunk line 1514, thereby to interrupt the previously traced holding circuit for energizing the winding of the relay R1530 in the paystation line circuit 1500, whereupon the latter relay restores. Upon restoring, the relay R1530 interrupts, at RA1531, a further point in the holding circuit for energizing the winding thereof, prepares, at RA1532, a point in the previously traced holding circuit for energizing in series the upper and lower windings of the relay R1520, interrupts, at RA1534 and RC1533, a point in the previously traced path for

5 applying ground potential to the control conductor C1512 of the trunk line 1510, and prepares at RA1534 and RC1535, a point in the previously mentioned path for applying battery potential at the lower winding of the relay R1540 to the control conductor C1512 of the trunk line 1510. The last-mentioned path extends, when completed, from battery at the lower winding of R1540 by way of the lower winding of R1540, 5

10 10 RC1535, RA1534, RC1525 and RA1523 to the control conductor C1512. This application of battery potential to the control conductor C1512 of the trunk line 1510 marks the paystation line circuit 1500 as idle to the switches having access thereto. Also, upon restoring, the relay R1530 15 prepares, at RA1536, a point in the previously traced path for applying ground potential to the start conductor C1550 extending to the common start and position distributor apparatus 330. 20

15 Furthermore, the relay R1530 interrupts, at RA1537 and RC1538, a point in the previously traced holding circuit for energizing in series the upper and lower windings of the relay R1520, thereby to cause the latter relay to restore and 25 prepares, at RA1537 and RC1539 a point in the previously traced original circuit for energizing the upper winding of the relay R1520.

Upon restoring, the relay R1520 interrupts, at 30 RA1523 and RC1524, a point in the previously traced path for applying ground potential to the control conductor C1512 of the trunk line 1510 and completes, at RA1523 and RC1525, the previously traced path for applying battery potential at the lower winding of the relay R1540 to the control conductor C1512 of the trunk line 1510. Further, the relay R1520 interrupts, at RA1521, 35 a point in the previously traced original circuit for energizing the relay R1530, interrupts, at RA1526 and RC1527, a further point in the previously traced path for applying ground potential to the start conductor C1550 extending to the common start and position distributor apparatus 330 and completes, at RA1526 and RC1528, the previously traced path for applying ground potential to the control conductor C1518 of the trunk line 1514. At this time the paystation line circuit 1500 is completely released and the paystation line 1501 is marked as idle to the switches having access thereto. 40

50 *Extension of a call from the distant exchange B to the switchboard*

A call which is to be extended from the distant exchange B to the central office A is routed by 55 the operator at the toll operator position in the distant exchange B by way of one of the toll lines to the central office A and is answered at the switchboard. For example, in order to route a call from the distant exchange B to the central office A by way of the toll line 340, the operator 60 at the toll operator position in the distant exchange B first seizes the toll line 340 and then causes ringing current to be projected thereover to the ring-down toll line circuit 310 individually 65 associated therewith. When the ringing current is projected over the toll line 340 to the ring-down toll line circuit 310 individually associated therewith, the line circuit operates to cause 70 ground potential to be applied to the control conductors of the trunk line 320, thereby to mark the trunk line 320 as busy to the switches having access thereto and to cause battery potential to be applied to the control conductors of the trunk line 321, thereby to mark the trunk line 321 as 75

a calling line. Also, the line circuit 310 operates to cause ground potential to be applied to the start conductor C311 extending to the common start and position distributor apparatus 330, thereby to cause the latter apparatus to operate 5 and assign one of the operator positions at the switchboard to answer the incoming toll call thereto, as previously explained.

Assuming that the operator at the first operator position 1400 is awaiting a call and has operated the talk key 780 of the finder switch 700 of the finder-selector link illustrated away from its normal position, thereby to condition the finder switch 700 to be operative to find a trunk line having a calling condition thereon, and that the common start and position distributor apparatus 330 10 operates and selects the first operator position 1400 as the position to which the incoming call to the switchboard is to be routed, the common start and position distributor apparatus 330 15 then operates to cause ground potential to be applied to the start conductor C1372 included in the cable 1374 extending to the first operator position, as previously explained. This application of ground potential to the start conductor C1372 completes the previously traced path for 20 applying ground potential to the conductor C1287 included in the cable 1286, thereby to complete the previously traced circuit for energizing the start relay R740 in the finder switch 700. When 25 the start relay R740 is thus energized, the finder switch 700 operates to find the trunk line having a calling condition thereon, as previously explained. At this time the trunk line 321 terminated in the main contact bank of the mechanism 35 701 included in the finder switch 700 and extending to the ring-down toll line circuit 310 has a calling condition thereon, as previously explained. Accordingly, the finder switch 700 operates to seize the trunk line 321. 40

As previously noted, the common start and position distributor apparatus 330 operates to mark, by way of the cable 185 in the vertical control contact bank 709 of the mechanism 701, the vertical level wherein the trunk line 321 is terminated. Also, the rotary position wherein the trunk line 321 is terminated is marked by the presence of battery potential appearing upon the control conductors of the trunk line 321 as previously noted. 50

Also, the common start and position distributor apparatus 330 operates to cause ground potential to be applied to the control conductor C1460 in the cable 1374 extending to the first operator position, thereby to complete an obvious circuit 55 for illuminating the toll answer lamp L1462. The illumination of the toll answer lamp L1462 indicates to the operator at the first operator position that the incoming call routed to her position is routed thereto over the toll line 340 from 60 the distant exchange B. 65

As previously noted, when the finder switch 700 operates to seize the trunk line 321, the electropolarized relay R710 therein operates to complete, at RA178, a path for short-circuiting the intermediate winding thereof, thereby to reduce the series resistance of a circuit extending by way of the control conductor of the trunk line 321 to the ring-down toll line circuit 310, thus causing the line circuit to operate further in a manner 70 more fully described subsequently. More specifically, the ring-down toll line circuit 310 operates at this time to remove ground potential from the start conductor C311 extending to the common start and position distributor apparatus 330, 75

thereby to cause the last-mentioned apparatus to be released as previously explained.

The operator at the first operator position 1400 then answers the call and communicates with the 5 operator at the toll operator position in the distant exchange B in order to ascertain the destination to which the call is to be extended. The operator at the first operator position, after learning the destination of the call, operates the sending key set 303 at her position in the previously described manner, thereby to cause the toll selector switch 800 to operate and extend the call to its destination as previously explained.

Also, it is noted that the operator at the operator 15 position in the distant exchange B may signal the operator at the first operator position 1400 when the talk key 780 of the finder switch 700 occupies either its normal or operated position. In order to signal the operator at the first 20 operator position, the operator at the toll operator position in the distant exchange B controls the ring-down toll line circuit 310 by way of the toll line 340 in order to cause the line circuit 310 to operate and apply ground potential to the control 25 conductor of the trunk line 321 terminated by the contact in the main contact bank of the mechanism 701 engaged by the wiper 706 of the wiper set of the mechanism 701. This application 30 of ground potential to the control conductor of the trunk line 321 completes the previously traced circuit for illuminating the supervisory lamp L767 in the event the talk key 780 of the finder switch 700 occupies its normal position; while this application of ground potential to the 35 control conductor of the trunk line 321 completes the previously traced circuit for energizing the supervisory relay R1230 in the relay group 1200A in the event the talk key 780 of the finder switch 700 occupies its operated position, as previously explained. When the supervisory relay 40 R1230 is thus energized, it operates to complete, at RA1231, the previously traced circuit for illuminating the supervisory lamp L767. The illumination of the supervisory lamp L767 indicates 45 to the operator at the first operator position that the operator at the toll operator position in the distant exchange B wishes to communicate with her, whereupon the operator at the first operator position communicates with the operator at the toll operator position in the distant exchange B.

The release of the connection between the distant exchange B and the switchboard, and the supervision and release of an established connection including the distant exchange B and 55 routed by way of the finder-selector link illustrated, is under the control of the operator at the first operator position 1400 and is accomplished in the previously described manner.

60 It is noted that when the finder switch 700 of the finder-selector link illustrated is released, the previously mentioned path for applying ground potential to the control conductor of the trunk line 321 is interrupted, thereby to cause the ring-down toll line circuit 310 individually associated with the trunk line 321 and the toll line 340 extending to the distant exchange B to operate and mark the trunk line 320 and the toll line 340 as idle to the switches having access thereto.

70 It is noted that each of the operator positions at the switchboard may be restricted to answering only toll calls from distant exchanges, such as the distant exchange B. For example, this may be accomplished at the first operator position 75 1400 by operating the toll answer key K10

away from its normal position to its right-hand position. When the toll answer key K10 is operated away from its normal position to its right-hand position, a point in the previously traced circuit for energizing the distributor start relay R1310 is interrupted, at the contact 1447 thereof, and an obvious path is completed, at the contact 1448 thereof, for applying battery potential to the control conductor C1450 included in the cable 1374 extending to the common start and position distributor apparatus 330. Also, at the contact 1448 of the toll answer key K10, the conductor C1453 included in the previously traced circuit for energizing the distributor start relay R1310 is connected to the control conductor C1451 included in the cable 1374 extending to the common start and position distributor apparatus 330. When the toll answer key K10 occupies its right-hand position, the circuit for energizing the distributor start relay R1310 is not completed immediately the operator at the first operator position operates the talk key 780 of the finder switch 700 away from its normal position and incident to the operation of the talk relay R1130, as previously explained, but the circuit for energizing the distributor start relay R1310 is only prepared, at RA1137 and RC1138, incident to the operation of the talk relay R1130.

The application of battery potential to the control conductor C1450 included in the cable 1374 extending to the common start and position distributor apparatus 330 causes the last-mentioned apparatus to operate and prevent ground potential from being applied to the start conductor C1372 included in the cable 1374 and extending to the first operator position 1400 when an incoming trunk call is extended to the switchboard. The common start and position distributor apparatus 330 is controlled, at this time, in such a manner that ground potential is applied to the start conductor C1372 included in the cable 1374 and extending to the first operator position only when a toll call is extended to the switchboard. Also, when a toll call is extended to the switchboard, the common start and position distributor apparatus 330 operates to cause battery potential to be applied to the control conductor C1451 included in the cable 1374 extending to the first operator position 1400, thereby to complete an alternative circuit for energizing the distributor start relay R1310. The last-mentioned auxiliary circuit extends, when completed, from ground at RA1101 by way of RA1137, RC1138, C1187, RA1273, RA1266, C1385, the winding of R1310, RA1321, C1453, the contact 55 1448 of the toll answer key K10, and the control conductor C1451 included in the cable 1374 extending to the common start and position distributor apparatus 330 to battery in the last-mentioned apparatus. When energized over the above-traced circuit, the distributor start relay R1310 operates in the previously described manner, thereby to cause the common start and position distributor apparatus 330 to select the first 60 operator position 1400 as the operator position to which the incoming call to the switchboard is to be extended and to cause the finder switch 700 of the finder-selector link illustrated to operate and route the incoming toll call to the first 65 operator position.

In order to reconvert the first operator position 1400 to a universal position so that both incoming toll and trunk calls to the switchboard may be answered thereat, it is only necessary to restore 70

the toll answer key K10 to its normal position. When the toll answer key K10 is thus restored to its normal position, a point is prepared, at the contact 1447 thereof, in the previously traced circuit for energizing the distributor start relay R1310, a point is interrupted, at the contact 1446 thereof, for applying battery potential to the control conductor C1450 included in the cable 1374 extending to the common start and position distributor apparatus 330, and the control conductor C1453 included in the previously traced circuit for energizing the distributor start relay R1310 is disconnected, at the contact 1448 thereof, from the control conductor C1451 included in the cable 1374 extending to the common start and position distributor apparatus 330.

Also, it is noted that the operator at any one of the operator positions at the switchboard may initiate operation of the finder switch of one of the finder-selector links associated with her position without regard to the operation of the common start and position distributor apparatus 330, thereby to cause the finder switch to operate and hunt for a trunk line having a calling condition thereon. For example, the operator at the first operator position 1400 may have the toll answer key K10 thereat operated, thereby to restrict the first operator position to the answering of incoming toll calls to the switchboard, and she may desire to assist the operators at the other operator positions by answering several calls without restoring the toll answer key K10 to its normal position. This may be accomplished by operating the release and start key K7 at the first operator position to its right-hand position, thereby to complete, at the contact 1434 thereof, an obvious path for applying ground potential to the control conductor C1458. This application of ground potential to the control conductor C1458 completes a path for energizing the start relay R740 in the finder switch 700 of the finder-selector link illustrated, assuming that the finder-selector link illustrated is in condition to receive an incoming call to the switchboard, the talk key 780 being operated away from its normal position at this time. The last-mentioned circuit extends from the grounded control conductor C1458 by way of RA1271, RC1262, RA1261, the conductor C1287 in the cable 1286, RA758 and the winding of R740 to battery. When energized over the above-traced circuit, the start relay R740 operates in the previously described manner, thereby to cause the finder switch 700 to operate and hunt for a trunk line terminated in the main contact bank of the mechanism 701 having a calling condition thereon.

Also, it is noted that when the finder switch 700 operates, as described above, the previously traced path for applying battery potential to the release conductor C1461 is completed incident to the operation of the switch-over relay R720 therein. This application of battery potential to the release conductor C1461 in the cable 1286 completes the previously traced circuit for energizing the winding of the answer pilot relay R1260, thereby to cause the latter relay to operate. Upon operating, the answer pilot relay R1260 interrupts, at RA1266, a point in the previously traced circuit for energizing the distributor start relay R1310, thereby to prevent operation of the latter relay at this time and, subsequently, to prevent the common start and position distributor apparatus from operating and routing an incoming toll call to the first operator position to be answered at this time.

Also, upon operating, the answer pilot relay R1260 completes, at RA1261 and RA1263, the previously traced holding circuit for energizing the winding of the start relay R740. Accordingly, it is only necessary for the operator at the first operator position 1400 to operate the release and start key K7 to its right-hand position momentarily and then return this key to its normal position in order to cause the finder switch 700 of the finder-selector link illustrated to operate independently of the common start and position distributor apparatus 330, as previously explained.

Extension of a call from the C. A. X. network to the switchboard

A call which is to be extended from one of the subscriber substations in the exchanges C, D and E to the central office A first is extended to one of the dual call control circuits and repeaters in the tandem exchange C and then routed by way of one of the C. A. X. trunks therefrom to the switchboard in the central office A to be answered. For example, a call initiated at the subscriber substation T3 in the tandem exchange C is first extended by way of the subscriber line 533 associated therewith to the line switch 520 individually associated with the subscriber line 533. The line switch 520 then operates automatically to select an idle selector switch, such, for example, as the selector switch 518 accessible thereto. The subscriber at the substation T3 then dials a predetermined number, thereby to cause the selector switch 518 to operate and seize a trunk line extending to an idle dual call control circuit and repeater in the tandem exchange C, such, for example, as the trunk line 503 extending to the dual call control circuit and repeater 500. When the trunk line 503 is seized by the selector switch 518, the dual call control circuit and repeater 500 operates, in a manner more fully described subsequently, thereby to initiate a call upon the C. A. X. trunk 510 extending to the C. A. X. trunk circuit 600 in the central office A.

Also, it is noted that a call initiated at a substation in the exchange D is first routed by way of a local switch train in the exchange D to a trunk line extending to the tandem exchange C, such, for example, as the trunk line 532. When the trunk line 532 is thus seized by the local switch train in the distant exchange D, the line switch 521 individually associated therewith operates to find a trunk line extending to an idle dual call control circuit and repeater in the tandem exchange C, such, for example, as the trunk line 503 extending to the dual call control circuit and repeater 500. When the trunk line 503 is thus seized, the dual call control circuit and repeater 500 operates, in a manner more fully described subsequently, thereby to extend a call over the C. A. X. trunk 510 to the C. A. X. trunk circuit 600 in the central office A, as previously noted.

Finally, it is noted that a call initiated at a substation in the exchange E is first routed by way of a local switch train in the exchange E to a trunk line extending to the tandem exchange C, such, for example, as the trunk line 531. When the trunk line 531 is thus seized by the local switch train in the distant exchange E, the line switch 522, individually associated therewith, operates to find a trunk line extending to an idle dual call control circuit and repeater in the tandem exchange C, such, for example, as the trunk line 503 extending to the dual call control circuit and repeater 500. When the trunk line 503

503 is thus seized, the dual call control circuit and repeater 500 operates, in a manner more fully described subsequently, thereby to extend a call over the C. A. X. trunk 510 to the C. A. X. trunk 5 circuit 60 in the central office A, as previously noted.

When the trunk line 503 extending to the dual call control circuit and repeater 500 is seized as previously noted, the dual call control circuit and 10 repeater 500 operates to apply ground potential to the control conductor of the trunk line 503, thereby to mark the trunk line 503 as busy to the switches having access thereto. Furthermore, the dual call control circuit and repeater 15 500 operates to apply battery potential to the control conductor C515 extending to the neutral point between the windings 513 and 514 connected across the line conductors C511 and C512 of the C. A. X. trunk 510, thereby to apply battery 20 potential to the end of the simplex link terminating in the tandem exchange C. Furthermore, it is noted that the simplex link mentioned includes the line conductors C511 and C512 of the C. A. X. trunk 510 and the windings 634 and 25 635 of the repeater 633 in the C. A. X. trunk circuit 600 disposed in the central office A. Also, it is noted that the neutral point between the windings 634 and 635 of the repeater 633 is connected to the control conductor C636. Accordingly, the 30 application of battery potential to the control conductor C515 causes battery potential to be applied by way of the simplex link to the control conductor C636 in order to conduct current from the dual call control circuit and repeater 500, by 35 way of the line conductors C511 and C512 of the C. A. X. trunk 510, in parallel to the control conductor C636.

This application of battery potential to the control conductor C636 completes a circuit for 40 energizing the relay R630 in the C. A. X. trunk circuit 600, the last-mentioned circuit extending from battery potential appearing upon the control conductor C636 by way of RA624, RC625, the winding of R630, RA610, RC618 and RA658 45 to ground at RC659. When energized over the above-traced circuit, the relay R630 operates to complete, at RA632, a circuit for energizing the winding of the start relay R640, this circuit extending from ground at RA617 by way of RA620, 50 RA632, RA656, RC657 and the winding of R640 to battery. When energized over the above-traced circuit, the start relay R640 operates to complete, at RA645 and RC646, a path for applying ground potential to the control conductor C684 of the 55 trunk line 680 extending to the C. A. X. trunk circuit 600, this path extending from ground at RC646 by way of RA645, RC616 and RA615 to the control conductor C684. This application of ground potential to the control conductor C684 60 of the trunk line 680 marks the C. A. X. trunk circuit 600 as busy to the switches having access thereto, thereby to prevent seizure of the trunk circuit 600 and the C. A. X. trunk 510 by the last-mentioned switches at this time. Also, upon 65 operating, the start relay R640 prepares, at RA644, a point in a path, traced hereinafter, for applying battery potential at the upper and lower windings of the marking relay R630 by way of the C. A. X. trunk distributor 202 to the control 70 conductor C673 of the trunk line 670 extending between the trunk circuit 600 and the finder switches of the finder-selector links having access thereto. Finally, the start relay R640 interrupts, at RA641 and RC642, an obvious path 75 for applying ground potential to the control con-

ductor C274 extending into the C. A. X. trunk distributor 202 and completes, at RC641 and RC643, an obvious path for applying ground potential to the control conductor C275 extending into the C. A. X. trunk distributor 202. This application of ground potential to the control conductor C275 completes a circuit for energizing the winding of the start relay R260 in the C. A. X. trunk distributor 202, provided the start relay R230 in the C. L. R. trunk distributor 201 is not operated at this time. The last-mentioned circuit extends from the grounded control conductor C275 by way of RA233 and the winding of R260 to battery. Shortly after the start relay R260 of the C. A. X. trunk distributor 202 is energized 15 over the above-traced circuit, it operates to interrupt, at RA261, a point in the previously traced circuit for energizing the start relay R230 in the C. L. R. trunk distributor 201. It is noted that the start relay R260 in the C. A. X. trunk distributor 202 is slow to operate; while the start relay R230 in the C. L. R. trunk distributor 201 is not slow to operate. Accordingly, incoming C. L. R. trunk calls are given preference over incoming C. A. X. calls due to the fact that the 20 operation of the start relay R230 prevents operation of the start relay R260 by interrupting, at RA233, a point in the above-traced energizing circuit for energizing the start relay R260, as 25 previously noted.

However, at this time, it is assumed that the C. L. R. trunk distributor 201 is not operating due to the fact that no C. L. R. trunk calls are waiting to be answered at the switchboard. Accordingly, at this time, the C. A. X. trunk distributor 30 202 begins to operate in order to assign incoming C. A. X. trunk calls to be answered, and further operation of the C. L. R. trunk distributor 201 is arrested until after all incoming C. A. X. trunk calls are answered at the switchboard, due to the 35 fact that the start relay R260 of the C. A. X. trunk distributor 202 remains in its operated condition until all such C. A. X. trunk calls are answered at the switchboard.

Also, upon operating, the start relay R260 prepares, at RA263, a point in a circuit, traced hereinafter, for energizing the lower winding of the relay R255 in series with the upper winding of the relay R250 and completes, at RA262, a circuit for energizing the lower winding of the relay 45 R250. The last-mentioned circuit extends from the grounded start conductor C275 by way of RA233, RA262, RA256 and the lower winding of R250 to battery. When energized over the above-traced circuit, the relay R250 operates to interrupt, at RA251, a point in a circuit, traced hereinafter, for energizing the upper winding of the relay R240 in series with the lower winding of the relay R255 and completes, at RA252, the previously mentioned circuit for energizing the upper winding thereof in series with the lower winding of the relay R255. The last-mentioned 50 circuit extends from ground at RA263 by way of the lower winding of RA255, RA246, RA252 and the upper winding of R250 to battery. When the lower winding of the relay R255 is energized over the above-traced circuit, it operates to interrupt, at RA256, a point in the previously traced circuit for energizing the lower winding of the relay R250, the latter relay being held in its operated 55 position at this time due to the completed circuit for energizing the upper winding thereof in series with the lower winding of the relay R255. Also, upon operating, the relay R255 completes, at 60 RC257, a holding circuit for energizing the upper 65 RC257, a holding circuit for energizing the upper 70 RC257, a holding circuit for energizing the upper 75 RC257, a holding circuit for energizing the upper 75

winding thereof, the last-mentioned circuit extending from the grounded start conductor C275 by way of RA233, RA262, RA251 and the upper winding of R255 to battery. Also, upon operating, the relay R250 prepares, at RA253, a point in a circuit, traced hereinafter, for energizing the lower winding of the relay R245, an additional point in the last-mentioned circuit being prepared at RA258 upon operation of the relay R255. Finally, upon operating, the relay R250 completes, at RA254, the previously mentioned path for applying battery potential to the control conductor C673 of the truck line 670 extending to the finder switches of the finder-selector links having access thereto. The last-mentioned path extends from battery at the upper winding of the marking relay R650, by way of the upper winding of R650, to RA652, and from the lower winding of R650, by way of the lower winding of R650, and RC653 to RA652, and from RA652 by way of RA644, C272, RA258 and C273 to the control conductor C673 of the truck line 670. Accordingly, it is noted that the operation of the relay R250 completes a path for marking the trunk line 670 extending to the first C. A. X. trunk circuit 600 as a calling line.

At this time it is noted that after the trunk line 670 is seized by the finder switch of one of the finder-selector links having access thereto, the start relay R640 in the C. A. X. trunk circuit 600 restores, in a manner more fully described subsequently, to interrupt, at RA641 and RC643, a point in the previously traced circuit for energizing the start relay R260 in the C. A. X. trunk distributor 202 and to complete, at RA641 and RC642, a circuit for energizing the relay R245 in the event a C. A. X. trunk call is waiting at this time to be answered. In the event another C. A. X. trunk call is waiting to be answered at this time, the circuit for energizing the start relay R260 in the C. A. X. trunk distributor 202 is completed therein, thereby to retain the latter relay in its operated position, and the previously mentioned circuit for energizing the relay R245 is completed incident to the restoration of the start relay R640 in the C. A. X. trunk circuit 600. The last-mentioned circuit extends from ground at RA641 by way of RA642, C274, RA258, RA253 and the lower winding of R245 to battery. When energized over the above-traced circuit, the relay R245 operates to complete, at RA247, a holding circuit for energizing the upper winding thereof in series with the lower winding of the relay R255, this circuit extending from ground at RA263 by way of the lower winding of R255, RA241, RA247 and the upper winding of R245 to battery. Also, upon operating, the relay R245 interrupts, at RA246, a point in the previously traced holding circuit for energizing the upper winding of the relay R250 in series with the lower winding of the relay R255, thereby to cause the relay R250 to restore. Finally, upon operating, the relay R245 prepares, at RA248, a point in a circuit for energizing the lower winding of the relay R240 and completes, at RA249, a path for marking the second C. A. X. trunk circuit as having a calling condition thereon.

Upon restoring, the relay R250 interrupts, at RA253, a point in the previously traced circuit for energizing the lower winding of the relay R245, the latter relay being retained in its operated position at this time due to the completed holding circuit for energizing the upper winding thereof in series with the lower winding of the relay R255. Also, upon restoring, the relay R250

interrupts, at RA252, a further point in the previously traced holding circuit for energizing the upper winding thereof in series with the lower winding of the relay R255 and prepares, at RA251, a point in a circuit, traced hereinafter, for energizing the upper winding of the relay R240 in series with the lower winding of the relay R255. Finally, the relay R250 interrupts, at RA254, a point in the path for marking the first C. A. X. trunk circuit 600 as having a calling condition thereon.

When the trunk line extending to the second C. A. X. trunk circuit is seized by the finder switch in one of the finder-selector links having access thereto, the second C. A. X. trunk circuit 15 operates to complete the previously mentioned circuit for energizing the lower winding of the relay R240, thereby to cause the latter relay to operate and complete, at RA242, the previously mentioned holding circuit for energizing the upper winding thereof in series with the lower winding of the relay R255, the last-mentioned circuit extending from ground at RA263 by way of the lower winding of R255, RA251, RA242 and the upper winding of R240 to battery. Also, 20 upon operating, the relay R240 interrupts, at RA241, a point in the previously mentioned holding circuit for energizing the upper winding of the relay R245 in series with the lower winding of the relay R255, thereby to cause the relay 25 R245 to restore. Also, upon operating, the relay R240 prepares, at RA243, a point in a circuit for energizing the lower winding of the relay R250 and completes, at RA244, a point in a path for marking the third C. A. X. trunk circuit as having a calling condition thereon.

Upon restoring, the relay R245 prepares, at RA246, a point in the previously traced holding circuit for energizing the upper winding of the relay R250 in series with the lower winding of the relay R255, interrupts, at RA247, a point in the previously traced holding circuit for energizing the upper winding thereof in series with the lower winding of the relay R255, and interrupts, at RA248, a point in the previously mentioned circuit for energizing the lower winding of the relay R240. Finally, the relay R245 interrupts, at RA249, a point in the previously mentioned path for marking the second C. A. X. trunk circuit as having a calling condition thereon.

The C. A. X. trunk distributor 202 operates, in the above-described manner, thereby to assign incoming C. A. X. trunk calls to be answered in a predetermined order at the switchboard. Also, it is noted that until all of the C. A. X. trunk calls are answered at the switchboard, the start relay R260 in the C. A. X. trunk distributor 202 remains in its operated position, thereby to retain interrupted, at RA261, the previously traced circuit for energizing the start relay R230 in the C. L. R. trunk distributor 201. Accordingly, at this time, all incoming C. A. X. trunk calls will be answered at the switchboard before any C. L. R. trunk calls will be answered 65 thereat.

Continuing now with the operation of the C. A. X. trunk distributor 202, upon operation of the start relay R260 thereof incident to the extension of the C. A. X. trunk call from the tandem exchange C to the C. A. X. trunk circuit 600, it is noted that, upon operating, the start relay R260 completes, at RA264, an obvious path for applying ground potential to the start conductor C271 extending to the common start and posi- 75

tion distributor apparatus 330. This application of ground potential to the start conductor C271 causes the common start and position distributor apparatus 330 to operate and route the call to one of the operator positions at the switchboard, as previously explained. Assuming that the operator at the first operator position 1400 is awaiting a call and has operated the talk key 780 of the finder switch 700 of the finder-selector link 700 illustrated away from its normal position, thereby to condition the finder switch 700 to be operative to find a trunk line having a calling condition thereon and that the common start and position distributor apparatus 330 operates and selects the first operator position 1400 as the position to which the incoming call to the switchboard is to be routed, the common start and position distributor apparatus 330 then operates to cause ground potential to be applied to the start conductor C1372 included in the cable 1374 extending to the first operator position 1400, as previously explained. This application of ground potential to the start conductor C1372 completes the previously traced path for applying ground potential to the conductor C1287 included in the cable 1286, thereby to complete the previously traced circuit for energizing the start relay R140 in the finder switch 700. When the start relay R140 is thus energized, the finder switch 700 operates to find the trunk line having a calling condition thereon in the previously described manner. At this time the trunk line 670 terminated in the main contact bank of the mechanism 701 included in the finder switch 700 and extending to the C. A. X. trunk circuit 600 has a calling condition thereon, as previously explained. Accordingly, the finder switch 700 operates to seize the trunk line 670.

As previously explained, the common start and position distributor apparatus 330 operates to mark, by way of the cable 765 in the vertical control contact bank 709 of the mechanism 701, the vertical level wherein the trunk line 670 is terminated. Also, the rotary position wherein the trunk line 670 is terminated is marked by the presence of battery potential appearing upon the control conductor C673 of the trunk line 670, the wiper 707 of the wiper set of the mechanism 701 engaging the contact in the main contact bank terminating the control conductor C673 of the trunk line 670 at this time.

Also, as previously noted, the common start and position distributor apparatus 330 operates to cause ground potential to be applied to the control conductor C1461' in the cable 1374 extending to the first operator position 1400, thereby to complete the previously traced circuit for illuminating the trunk answer lamp L1463. The illumination of the trunk answer lamp L1463 indicates to the operator at the first operator position 1400 that the incoming call which has been extended thereto is a trunk call. More specifically, the trunk answer lamps at the first operator position 1400 are so connected and arranged that the illumination of the trunk answer lamp L1463 indicates to the operator at the first operator position that the incoming call is from the C. A. X. network.

As previously noted, when the finder switch 700 operates to seize the trunk line 670, the electropolarized relay R710 therein operates to complete, at RA718, an obvious path for short-circuiting the intermediate winding thereof, thereby to reduce the series resistance of a circuit, traced hereinafter, for energizing in multiple the upper

and lower windings of the marking relay R650 in the C. A. X. trunk circuit 600. The last-mentioned circuit extends from ground at RA726 by way of RC721, RA718, the wiper 707 of the wiper set of the mechanism 701, the control conductor C673 of the trunk line 670, C273, RA254, C272 and RA644 to RA652, and from RA652 by way of the upper winding of R650 to battery, and from RA652 by way of RC653 and the lower winding of R650 to battery. When energized over the above-traced circuit, the marking relay R650 operates to complete, at RA651 and RA652, a holding circuit for energizing the upper winding thereof, this circuit extending from the grounded control conductor C673 of the trunk line 670 by way of RA651, RA652 and the upper winding of R650 to battery. Also, upon operating, the marking relay R650 interrupts, at RA652 and RC653, a point in the previously traced circuit for energizing the lower winding thereof, prepares, at 20 RA654 and RC654, a point in a path, traced hereinafter, for applying ground potential to the control conductor C684 of the trunk line 680, and interrupts, at RA656 and RC657, a point in the previously traced circuit for energizing the start 25 relay R640, thereby to cause the latter relay to restore.

Upon restoring, the start relay R640 interrupts, at RA641 and RC643, the previously traced path for applying ground potential to the start conductor C275, thereby to interrupt the previously traced circuit for energizing the winding of the start relay R260 in the C. A. X. trunk distributor 202 in the event no other C. A. X. trunk calls are waiting to be answered at this time. 35 Also, upon restoring, the start relay R640 completes, at RA641 and RC642, the previously traced path for applying ground potential to the control conductor C274, thereby to complete the previously traced circuit for energizing the lower 40 winding of the relay R245 in the C. A. X. trunk distributor 202 in the event another C. A. X. trunk call is waiting to be answered at this time, as previously explained. Also, the start relay R640 interrupts, at RA644, a further point in 45 the previously traced circuit for energizing the lower winding of the marking relay R650, interrupts, at RA645 and RC646, a point in the previously traced path for applying ground potential to the control conductor C684 of the 50 trunk line 680, and completes, at RA645 and RC647, the previously mentioned path for applying ground potential to the control conductor C684. The last-mentioned path extends from ground at RC654 by way of RA654, RC647, 55 RA645, RC646 and RA645 to the control conductor C684. This application of ground potential to the control conductor C684 of the trunk line 680 marks the trunk circuit 600 as busy to the switches having access thereto, as previously 60 noted.

At this time, in the event another C. A. X. trunk call is waiting to be answered, the start relay R260 in the C. A. X. trunk distributor 202 remains in its operated position, and the C. A. X. 65 trunk distributor 202 operates in the previously described manner. However, in the event no other C. A. X. trunk call is waiting to be answered at this time, the start relay R260 restores to interrupt, at RA262, a further point in the 70 previously traced circuit for energizing the lower winding of the relay R250 and to interrupt, at RA263, a point in the previously traced holding circuit for energizing the upper winding of the relay R250 in series with the lower winding of 75

the relay R255, thereby to cause the latter relays to restore. Also, the start relay R260 interrupts, at RA264, the previously mentioned path for applying ground potential to the start conductor C274 extending to the common start and position distributor apparatus 330, thereby to arrest further operation of the last-mentioned apparatus. Finally, the start relay R260 prepares, at RA261, a point in the previously traced circuit for energizing the start relay R230 in the C. L. R. trunk distributor 201, thereby to condition the C. L. R. trunk distributor 201 to be operative in order to cause C. L. R. trunk calls to be routed to the switchboard to be answered.

Furthermore, it is noted that, upon operating, the marking relay R650 in the C. A. X. trunk circuit 600 prepares, at RA656 and RC656, a point in a path for applying ground potential to the control conductor C675 of the trunk line 670, this path extending, when completed, from ground at RA617 by way of RA620, RA632, RA656 and RC656 to the control conductor C675. This application of ground potential to the control conductor C675 completes an obvious path for short-circuiting the winding of the relay R660 and completes a circuit for energizing the winding of the supervisory relay R1230 in the relay group 1200A. The last-mentioned circuit extends from the grounded control conductor C675 of the trunk line 670 by way of the wiper 706 of the wiper set of the mechanism 701, RA117, RA144, RA143, the conductor C1383 in the cable 1286, RA1346, RC1348, C1384, RA1227, RC1229, the resistor 1232, and the winding of R1230 to battery. When energized over the above-traced circuit, the supervisory relay R1230 operates to complete, at RA1231, the previously traced circuit for illuminating the supervisory lamp L767.

Also, upon operating, the marking relay R650 in the C. A. X. trunk circuit 600 interrupts, at RA658 and RC659, a point in the previously traced circuit for energizing the relay R630, thereby to cause the latter relay to restore, and completes, at RA658 and RC658, a path for applying battery potential to the control conductor C636 connected to the simplex link including the C. A. X. trunk 510. The last-mentioned path extends from battery at the resistor 685, by way of the resistor 685, RC658, RA658, RC618, RA610, the winding of R630, RC625 and RA624 to the control conductor C636.

Upon restoring, the relay R630 interrupts, at RA632, a point in the previously traced path for applying ground potential to the control conductor C675 of the trunk line 670, thereby to interrupt the previously traced circuit for energizing the supervisory relay R1230 in the relay group 1200A. The relay R660 in the C. A. X. trunk circuit 600 operates at this time; however, the supervisory relay R1230 in the relay group 1200A does not operate in series circuit relationship with the relay R660 due to the high series resistance of this circuit.

At this time a connection is established between the dual call control circuit and repeater 500 in the tandem exchange C and the first operator position 1400, the line conductors C505 and C506 of the trunk line 504 extending to the dual call control circuit and repeater 500 being capacitively coupled to the line conductors C511 and C512, respectively, of the C. A. X. trunk 510 by the condensers 507 and 508, respectively. Also, the line conductors C511 and C512 of the C. A. X. trunk are operatively connected together

by way of the windings 634 and 635 of the repeater 633, while the last-mentioned windings of the repeater 633 are operatively connected with the windings 637 and 639 thereof, the last-mentioned windings of the repeater 633 being included in the loop circuit extending to the first operator position 1400. More specifically, the wiper 702 of the wiper set of the mechanism 701 engages the contact in the main contact bank of the mechanism 701 terminating the line conductor C761 of the trunk line 670; and the wiper 703 of the wiper set of the mechanism 701 engages the contact in the main contact bank of the mechanism 701 terminating the line conductor C672 of the trunk line 670. Also, the line conductors C671 and C672 of the trunk line 670 are operatively connected to the repeater 633, the line conductor C671 being connected by way of RA622, RC623, the winding 637, the condenser 638, the winding 639, RC628 and RA627 to the line conductor C672. It is noted that the wipers 702 and 703 of the wiper set of the mechanism 701 are operatively connected with the line conductors of the trunk circuit at the first operator position 1400, as previously explained. Finally, it is noted that the line conductors C505 and C506 of the trunk line 505 extending to the dual call control circuit and repeater 500 are operatively associated with the line conductors of the trunk line 503 in the dual call trunk circuit and repeater 500, thereby operatively to connect the telephone instrument at the subscriber substation operatively associated with the trunk line 503 to the first operator position 1400.

The operator at the first operator position 1400 then answers the call and communicates with the subscriber at the calling substation in the C. A. X. network in order to ascertain the destination to which the call is to be extended. The operator at the first operator position, after learning the destination of the call, operates the sending key set 303 at her position, in the previously described manner, thereby to cause the toll selector switch 800 to operate and extend the call to its destination, as previously explained.

In connection with the supervision of the connection between the C. A. X. network and the first operator position, it is noted that the subscriber at the calling subscriber substation in the C. A. X. network has switchhook supervision 50 and when he replaces the receiver of the telephone instrument at his substation upon its hook, the supervisory lamp L767 is illuminated regardless of the position of the talk key 780 of the finder switch 700. More particularly, when the subscriber at the calling subscriber substation replaces the receiver of the telephone instrument thereat upon its hook, the dual call control circuit and repeater 500 is controlled, by way of the trunk line 503, to cause ground potential to be applied to the control conductor C515 connected to the simplex link including the C. A. X. trunk 510, thereby to cause ground potential to be applied to the control conductor C636 connected to the simplex link. This application of ground potential to the control conductor C636 completes a circuit for energizing the relay R630 in the C. A. X. trunk circuit 600, the last-mentioned circuit extending from ground potential upon the control conductor C636 by way of RA624, RC625, the winding of R630, RA610, RC618, RA658, RC658 and the resistor 685 to battery. When energized over the above-traced circuit, the relay R630 operates to complete, at RA632, the previously traced path for applying

ground potential to the control conductor C675 of the trunk line 670 in order to cause ground potential to be applied to the wiper 706 of the wiper set of the mechanism 701, as previously explained. This application of ground potential to the wiper 706 of the wiper set of the mechanism 701 completes the previously traced circuit for illuminating the supervisory lamp L767 in the event the talk key 780 of the finder switch 700 occupies its normal position; while this application of ground potential to the wiper 706 completes the previously traced circuit for energizing the supervisory relay R1230 in the relay group 1200A in the event the talk key 780 of the finder switch 700 is operated away from its normal position at this time. Upon operating, the supervisory relay R1230 completes, at RA1231, the previously traced circuit for illuminating the supervisory lamp L767. The illumination of the supervisory lamp L767 indicates to the operator at the first operator position that the subscriber at the calling substation in the C. A. X. network has replaced the receiver of the telephone instrument at his substation upon its hook.

Also, it is noted that when the connection between the subscriber substation in the C. A. X. network and the switchboard is released, due to the release of the finder switch 700, the previously traced path for applying ground potential to the control conductor C673 of the trunk line 670 is interrupted, thereby to interrupt the previously traced holding circuit for energizing the upper winding of the marking relay R650 in the C. A. X. trunk circuit 600, whereupon the latter relay restores. Upon restoring, the marking relay R650 interrupts, at RA651, a further point in the previously traced circuit for energizing the winding thereof, interrupts, at RA654 and RC654, the previously traced path for applying ground potential to the control conductor C684 of the trunk line 680, and completes, at RA654 and RC655, a point in a circuit, traced hereinafter, for applying battery potential to the control conductor C684. This application of battery potential to the control conductor C684 of the trunk line 680 marks the C. A. X. trunk circuit 600 as idle to the switches having access thereto. Also, the marking relay R650 interrupts, at RA656 and RC656, a further point in the previously traced path for applying ground potential to the control conductor C675 of the trunk line 670, prepares, at RA656 and RC657, a point in the previously traced circuit for energizing the start relay R640, interrupts, at RA658 and RC658, a point in the previously traced path for applying battery potential to the control conductor C636 connected to the simplex link, and completes, at RA658 and RC659, a point in the previously traced path for applying ground potential to the control conductor C636 connected to the simplex link. At this time the C. A. X. trunk circuit 600 is completely released. The release of the apparatus in the C. A. X. network is effected, in the usual manner, when battery potential is removed from the control conductor C636 and ground potential is applied thereto, the ground potential applied to the control conductor C636 being forwarded by way of the simplex link to the control conductor C515 extending to the dual call control circuit and repeater 500.

Extension of a call from the switchboard to a local subscriber substation in the central office A

Assuming that an incoming call answered at 75 one of the operator positions at the switchboard,

such, for example, as the first operator position 1400, is to be extended to a local subscriber substation in the central office A, such, for example, as the local subscriber substation T1, the operator at the first operator position initiates the extension of the call by actuating the sending key set 303 as previously noted. Assuming that the incoming call has been answered at the first operator position and routed thereby by way of the finder switch 700 of the finder-selector link 100 illustrated and that the sender control circuit 300 is operatively associated with the cable 786 individually extending to the toll selector switch 800 and with the digit register and control circuit 304, the operator at the first operator position 15 actuates the keys of the sending key set 303, thereby to cause the digit register and control circuit 304 to register a series of digits corresponding to the directory number of the local subscriber substation T1. The digit register and control circuit 304 then operates to control the operation of the sender control circuit 300, thereby to cause the sender control circuit 300 to transmit the impulses comprising the digits of the directory number to the toll selector switch 25 800 in a well-known manner. At this time the normally completed circuit for energizing the upper and lower windings of the line relay R820 in the toll selector switch 800 is interrupted, in the sender control circuit 300, a number of times 30 corresponding to the first digit of the directory number of the local subscriber substation T1, thereby to cause the line relay R820 to restore repeatedly a number of times corresponding to the number of interruptions of the circuit for 35 energizing the upper and lower windings thereof. The repeated restoration of the line relay R820 is effective to complete repeatedly, at RA822 and RC824, the previously traced circuit for energizing the vertical magnet M801 of the 40 mechanism 801, thereby to cause the vertical magnet M801 to operate repeatedly to drive the wiper set of the mechanism 801 in the vertical direction to a corresponding level in the associated main contact bank.

Assuming that the group of trunk lines including the trunk line 950 extending to the trunk circuits associated with the local connector switches is terminated in the main contact bank of the mechanism in one of the first three levels 45 thereof, the selector switch 800 operates, in the previously described manner, at the conclusion of the first digit transmitted thereto. More specifically, the rotary magnet M802 of the mechanism 801 operates automatically to drive the 50 wiper set of the mechanism in the rotary direction until the wiper set engages a contact set in the main contact bank of the mechanism terminating a trunk line extending to an idle one of the trunk circuits previously mentioned. Assuming that the trunk circuit 900 is the first idle 60 trunk circuit in the group, the toll selector switch 800 operates automatically, in the previously described manner, thereby to seize the trunk line 950 extending thereto.

It is noted that subsequent to the first digit transmitted to the toll selector switch 800, and while the wiper set thereof is being driven in the radial direction by the rotary magnet M802 of the mechanism 801, the relay R850 occupies 70 its operated position, thereby to retain completed, at RA850, the previously traced path for applying battery potential at the resistor 827 to the control conductor C789 of the trunk line 793 extending to the toll selector switch 800. This 75

application of battery potential by way of the resistor 827 to the control conductor C789 of the trunk line 793 prevents further operation of the sender control circuit 300 until subsequent 5 to the operation of the toll selector switch 800 to seize the trunk line 950 extending to the trunk circuit 900, thereby to prevent the second and additional digits from being transmitted to the toll selector switch 800 while this switch is operating to hunt for a trunk line extending to an idle one of the trunk circuits including the trunk circuit 900, as previously explained.

The trunk circuit 900 is marked as idle by the presence of battery potential upon the control conductor C954 of the trunk line 950, thereby to cause the upper winding of the electropolarized relay R810 in the toll selector switch 800 to be energized when the wiper set of the mechanism 801 engages the contact set in the main contact bank thereof terminating the trunk line 950, as previously explained. The battery potential appearing upon the control conductor C954 of the trunk line 950 is derived in the local connector switch 960 individually associated with the trunk 25 circuit 900 and is forwarded to the control conductor C954 of the trunk line 950 by way of a path extending from the control conductor C958 of the trunk line 955 extending into the local connector switch 960 by way of RA931 and RC933 to the control conductor C954 of the trunk line 950. When the upper winding of the electropolarized relay R810 in the toll selector switch 800 is energized, the latter relay operates as previously explained, thereby to complete, at 30 RA815, the previously traced path for applying ground potential to the wiper 805 of the wiper set of the mechanism 801. This application of ground potential to the wiper 805 of the wiper set of the mechanism 801 causes ground to be forwarded by way of the control conductor C954 of the trunk line 950, RC933, RA931 and the control conductor C958 of the trunk line 955 to the local connector switch 960. When ground potential is thus forwarded to the local connector switch 960, this switch is rendered operative 40 in response to impulses transmitted thereto. Also, upon operating, the electropolarized relay R810 completes, at RA811 and RC812 and at RA813 and RC814, the previously traced paths 45 for connecting the line conductors C787 and C788 of the trunk line 793 to the wipers 802 and 803, respectively, of the wiper set of the mechanism 801. Also, it is noted that the wiper 802 of the wiper set of the mechanism 801 is connected by way of the line conductor C951 of the trunk line 950, RA922 and RC921 to the line conductor C956 of the trunk line 955; and the wiper 803 of the wiper set of the mechanism 801 is connected by way of the line conductor C952 of the trunk line 950, RA924 and RC923 to the line conductor C957 of the trunk line 955. When the local connector switch 960 operates, as previously explained, a loop circuit is completed therein between the line conductors C956 and C957 of the trunk line 955 over which subsequent impulses transmitted from the sender control circuit 300 are conducted.

Also, upon operating, the electropolarized relay R810 in the toll selector switch 800 causes the relay R850 therein to restore, thereby to interrupt, at RA850, the previously traced path for applying battery potential by way of the resistor 827 to the control conductor C789 of the trunk line 793, in order to render the sender control circuit 300 again operative to transmit

the second and subsequent digits registered in the digit register and control circuit 304. The sender control circuit 300 then operates to transmit the second and third digits mentioned over the cable 786, the toll selector switch 800, and 5 the trunk circuit 900 to the local connector switch 960, thereby to cause the connector switch 960 to operate and seize the trunk line 963 extending to the line circuit 961 individually associated with the subscriber line 962 extending to 10 the called subscriber substation T1. The subsequent operation of the local connector switch 960 depends upon the idle or busy condition of the subscriber line 962, as will be explained more fully hereinafter. After all of the digits have 15 been transmitted by the sender control circuit 300 to the local connector switch 960, the sender control circuit 300 operates to cause ground potential to be applied to the conductor C791 in the cable 786, thereby to complete the previously 20 traced circuit for energizing the upper winding of the cut-through relay R760 in the finder switch 700, as previously explained. The sender control circuit 300 is then automatically released, as previously noted.

When the previously traced circuit for energizing the upper winding of the cut-through relay R760 is completed, the latter relay operates to complete, at RA765, the previously traced holding circuit for energizing the lower winding thereof and to complete, at RA761 and RA762, the previously traced connection between the line conductors C787 and C788 of the trunk line 793 extending to the toll selector switch 800 and the trunk circuit at the first operator position, thereby operatively to connect the first operator position 1400 and the local connector switch 960. Also, at RA763, the cut-through relay R760 completes a circuit for energizing the winding of the relay R1120 in the relay group 1200A in series 35 with the upper winding of the relay R920 in the trunk circuit 900. The last-mentioned circuit extends from ground at the upper winding of the relay R920, by way of the upper winding of R920, RC926, RA926, the control conductor C953 of the 40 trunk line 950, the wiper 804 of the wiper set of the mechanism 801, RA871, the control conductor C789 of the trunk line 793, RA763, the contact 714 of the talk key 780, the conductor C1284 in the cable 1286, RA1217, RC1219, C1185, the resistor 1122 and the winding of R1120 to battery. When energized over the above-traced circuit, the relay R1120 operates to complete, at RA1121, the previously mentioned path for short-circuiting the resistor 1122, thereby to reduce the series 50 resistance of the above-traced circuit, whereupon the relay R920 in the trunk circuit 900 operates. Also, when the series resistance of the above-traced circuit is thus reduced, the supervisory lamp L776 is illuminated, thereby to indicate to 55 the operator at the first operator position that the local connector switch 960 has operated to seize the trunk line 963 extending to the line circuit 961 individually associated with the subscriber line 962. Also, upon operating, the cut-through relay R760 in the finder switch 700 completes, at RA764, the previously traced path for applying ground potential to the control conductor C790 of the trunk line 793, thereby to complete the previously traced holding circuit for energizing the intermediate winding of the electropolarized relay R810 in the toll selector switch 800.

Upon operating, the relay R920 in the trunk circuit 900 completes, at RA928, an obvious holding circuit for energizing the lower winding there-

- of from the grounded control conductor C954 of the trunk line 950, ground potential being applied to the control conductor C954 at the wiper 805 of the wiper set of the mechanism 801 of the toll selector switch 800. Also, upon operating, the relay R920 completes, at RA928, an obvious circuit for energizing the winding of the relay R930, thereby to cause the latter relay to operate and complete, at RA931 and RC932, an obvious path 10 for applying ground potential to the control conductor C958 of the trunk line 955 extending to the local connector switch 960. This application of ground potential to the control conductor C958 of the trunk line 955 retains the local connector switch 960 in its operated position. Also, the relay R920 interrupts, at RA922 and RC921 and at RA924 and RC923, points in the previously traced metallic connection between the line conductors C951 and C952 of the trunk line 950 and the line conductors C956 and C957 of the trunk line 955, completes, at RA921 and RA922 and at RA923 and RA924, a connection between the repeater 910 and the line conductors C951 and C952 of the trunk line 950, and completes, at RA925, a connection between the line conductors C956 and C957 of the trunk line 955 in the repeater 910. More particularly, the line conductor C951 of the trunk line 950 is connected by way of RA922, RA921, the winding 912, the condenser 916, the winding 914, RA923 and RA924 to the line conductor C952 of the trunk line 950; and the line conductor C956 of the trunk line 955 is connected by way of the winding 911, the condenser 915, the winding 913 and RA925 to the line conductor C957 of the trunk line 955. Also, it is noted that the upper winding of the relay R940 is bridged across the condenser 915, thereby to complete a circuit for energizing the upper winding thereof, a circuit for energizing the lower winding thereof 40 having been completed, at RA928, upon operation of the relay R920.

The relay R940 is of the differential type and when the upper winding thereof is energized in a predetermined direction, the lower winding thereof having previously been energized, this relay operates to complete, at RA941, a path for applying ground potential to the control conductor C953 of the trunk line 950. The last-mentioned path extends from the grounded control conductor C954 of the trunk line 950 by way of RA928, RA941, RC927 and RA926 to the control conductor C953. This application of ground potential to the control conductor C953 of the trunk line 950 completes the previously traced circuit 50 for illuminating the supervisory lamp L776, as previously noted.

The windings 912, 914 of the repeater 910 are operatively associated with the windings 911, 913, thereby operatively to associate the trunk line 950 with the trunk line 955. At this time the trunk circuit at the first operator position 1400 is operatively associated with the connector switch 960 and the connector switch 960 operates to test the idle or busy condition of the subscriber line 962. 60 In the event the subscriber line 962 is busy, the local connector switch 960 operates to cause busy tone current to be returned over the trunk line 955 to the repeater 910, this busy tone current being repeated by the repeater 910 to the trunk circuit at the first operator position, thereby to cause the receiver of the telephone instrument thereat to be actuated to produce busy tone. The operator at the first operator position then advises the calling subscriber that the desired connection 70 may not immediately be had due to the

busy condition of the called subscriber substation T1. The operator at the first operator position then releases the front end of the connection including the toll selector switch 800, the trunk circuit 800 and the connector switch 960 in a manner more fully described hereinafter. Subsequently, the operator at the first operator position may again set up the connection to the local connector switch 960, thereby again to test the idle or busy condition of the called subscriber substation T1. Finally, the called subscriber substation T1 is found to be idle, or the calling subscriber is advised to abandon the call.

In the event the called subscriber substation T1 is idle at this time, the local connector switch 960 15 operates to cause ringing current to be projected over the subscriber line 962 to the called subscriber substation T1. A portion of this ringing current projected over the subscriber line 962 is returned over the trunk line 955 and repeated by 20 the repeater 910 to the trunk circuit at the first operator position, in the usual manner, thereby to indicate to the operator thereat that the called subscriber substation T1 is being rung. When the subscriber at the called substation T1 answers 25 the call, the local connector switch 960 switches through, thereby operatively to connect the repeater 910 and the telephone instrument at the called substation T1.

The operator at the first operator position 1400 30 then converses with the subscriber at the called substation T1, advising him that there is an incoming call at the board for him. The operator at the first operator position may disconnect the relay group 1200A from the finder-selector link 35 illustrated by operating the talk key 780 away from its normal position as previously explained.

When the local connector switch 960 switches through, when the call is answered at the called subscriber substation T1, as previously noted, 40 battery is reversed over the trunk line 955, thereby to cause the upper and lower windings of the differential relay R940 to be energized in opposite directions, whereupon the relay R940 restores. Upon restoring, the relay R940 interrupts, at 45 RA941, a point in the previously traced circuit for illuminating the supervisory lamp L776. Moreover, it is noted that the subscriber at the called subscriber substation T1 has switch hook supervision and may signal the operator at the first operator position 1400 by intermittently operating the switch hook at his substation, thereby to cause battery potential to be intermittently reversed over the trunk line 955, whereupon the relay R940 intermittently operates. Each time the relay R940 50 operates, it completes, at RA941, the previously traced path for applying ground potential to the control conductor C953 of the trunk line 950. Each time the relay R940 restores, it interrupts, 60 at RA941, the previously traced path for applying ground potential to the control conductor C953 of the trunk line 950. This application of ground potential to the control conductor C953 of the trunk line 950 completes one of the previously traced circuits for illuminating the supervisory lamp L776, depending upon the position of the talk key 780 of the finder switch 100, thereby to cause the supervisory lamp L776 to flash. The flashing of the supervisory lamp L776 indicates to the operator at the first operator position that the subscriber at the called substation T1 desires her attention, whereupon the operator at the first operator position communicates with the subscriber at the substation T1.

The supervision and the release of the established connection routed by way of the finder-selector link illustrated are accomplished in the manner previously described. It is noted that when the established connection is released, the toll selector switch 800 is returned to its normal position, whereupon the previously traced path for applying ground potential to the control conductor C954 of the trunk line 950 is interrupted, thereby to cause the relays R920, R930 and R940 in the trunk circuit 990 to restore. Upon restoring, the relay R920 interrupts, at RA921 and RA922 and at RA923 and RA924, the previously traced connection between the trunk line 950 and the repeater 910 and completes, at RA922 and RC921 and at RA924 and RC923, the previously traced metallic connection between the trunk lines 950 and 955. Also, upon restoring, the relay R920 interrupts, at RA928, a further point in the holding circuit for energizing the lower winding thereof and completes, at RA926 and RC926, the previously traced path for applying ground potential, at the upper winding of R920, to the control conductor C953 of the trunk line 950. Upon restoring, the relay R940 interrupts, at RA941, a point in the previously traced path for connecting ground potential upon the control conductor C954 to the control conductor C953 of the trunk line 950. Upon restoring, the relay R930 interrupts, at RA931 and RC932, a point in the path for applying ground potential to the control conductor C958 of the trunk line 955 extending to the local connector switch 960 and completes, at RA931 and RC933, the previously mentioned connection between the control conductor C954 of the trunk line 950 and the control conductor C958 of the trunk line 955. When ground potential is removed from the control conductor C958 of the trunk line 955, the local connector switch 960 is caused to release, in the usual manner, thereby to cause the line circuit 961 individually associated with the subscriber line 962 to operate and mark the subscriber line 962 as idle, assuming that the subscriber at the substation T1 has replaced the receiver of the telephone instrument thereat upon its hook at this time.

Extension of a call from the switchboard to a paystation in the central office A

Assuming that an incoming call answered at one of the operator positions at the switchboard, such, for example, as the first operator position 1400, is to be extended to a local paystation in the central office A, such, for example, as the local paystation T2, the operator at the first operator position initiates the extension of the call by actuating the sending key set 303, as previously noted. Assuming that the incoming call has been answered at the first operator position and routed thereto by way of the finder switch 700 of the finder-selector link illustrated and that the sender control circuit 300 is operatively associated with the cable 786 individually extending to the toll selector switch 800 and with the digit register and control circuit 304, the operator at the first operator position actuates the keys of the sending key set 303, thereby to cause the digit register and control circuit 304 to register a series of digits corresponding to the directory number of the local paystation T2. The digit register and control circuit 304 then operates to control the operation of the sender control circuit 300, thereby to cause the sender control circuit 300 to transmit the impulses comprising the digits of the di-

rectory number to the toll selector switch 800 in a well-known manner.

The impulses comprising the first digit of the directory number of the called paystation T2 are transmitted from the sender control circuit 300 to the toll selector switch 800, in the previously described manner, thereby to cause the wiper set of the mechanism 801 of the toll selector switch 800 to be driven in the vertical direction to a corresponding level, as previously explained. 10

Assuming that the group of trunk lines including the trunk line 1080 extending to the trunk circuits associated with the combined local and toll connector switches is terminated in the main contact bank of the mechanism in one of the first three levels thereof, the selector switch 800 operates, in the previously described manner, at the conclusion of the first digit transmitted thereto. More specifically, the wiper set of the mechanism 801 is driven in the rotary direction 15 until it engages a contact set in the main contact bank of the mechanism terminating a trunk line extending to an idle one of the trunk circuits previously mentioned. Assuming that the trunk circuit 1000 is the first idle trunk circuit in this group, the toll selector switch 800 operates, in the previously described manner thereby to seize the trunk line 1080 extending thereto. As previously noted, the toll selector switch 800 operates to prevent the second and additional digits 20 from being transmitted thereto while it is operating to find a trunk line extending to an idle one of the trunk circuits mentioned, such, for example, as the trunk line 1080 extending to the 25 trunk circuit 1000. 30

35 The trunk circuit 1000 is marked as idle by the presence of battery potential upon the control conductor C1080 of the trunk line 1080, thereby

40 to cause the upper winding of the electropolarized relay R810 in the toll selector switch 800 to be energized when the wiper set of the mechanism 801 engages the contact set in the main contact bank of the mechanism 801 terminating the trunk line 1080, as previously explained. The battery potential appearing upon the control conductor 45 C1080 of the trunk line 1080 is derived in the trunk circuit 1000 and extends from the winding of the relay R1030, by way of the winding of R1030, RC1023 and RA1021 to the control conductor S1080. When the upper winding of the 50 electropolarized relay R810 in the toll selector switch 800 is energized, the latter relay operates, as previously explained, thereby to complete, at RA815, the previously traced path for applying ground potential to the wiper 805 of the wiper 55 set of the mechanism 801. This application of ground potential to the wiper 805 of the wiper set of the mechanism 801 causes ground potential to be forwarded by way of the control conductor C1080 of the trunk line 1080 into the trunk circuit 1000, thereby to complete a circuit for energizing the winding of the relay R1030 therein, this circuit extending from the grounded control conductor C1080 of the trunk line 1080 by way of RA1021, RC1023 and the winding of R1030 to 60 C5 battery. When energized over the above-traced circuit, the relay R1030 operates to complete, at RA1031, a path for applying ground potential to the control conductor C1087 of the trunk line 1084 extending into the combined local and toll connector switch 1090, the last-mentioned path extending from ground at RA1031 by way of RA1062 to the control conductor C1087. This application of ground potential to the control conductor C1087 prepares a circuit in the combined 65

70 75 connector switch 1090, the last-mentioned path extending from ground at RA1031 by way of RA1062 to the control conductor C1087. This application of ground potential to the control conductor C1087 prepares a circuit in the combined 75

local and toll connector switch 1090 for projecting ringing current over a trunk line seized thereby subsequent to the operation thereof. Also, upon operating, the relay R1030 interrupts, at RA1032 and RC1034, a point in a circuit for energizing the winding of the relay R1020 and completes, at RA1032 and RC1033, an obvious path for applying ground potential to the control conductor C1088 of the trunk line 1084 extending to the combined local and toll connector switch 1090. This application of ground potential to the control conductor C1088 of the trunk line 1084 marks the combined local and toll connector switch 1090 as busy to the selector switches of the local switch train having access thereto. Also, it is noted that when the combined local and toll connector switch 1090 is seized by a selector switch in the local switch train, ground potential therein is applied to the control conductor C1088 of the trunk line 1084, thereby to complete the previously mentioned circuit for energizing the relay R1020, the last-mentioned circuit extending, when completed, from the grounded control conductor C1088 of the trunk line 1084 by way of RA1032, RC1034 and the winding of R1020 to battery. When energized over the above-traced circuit, the relay R1020 operates to interrupt, at RA1021 and RC1023, a point in the previously traced path for applying battery potential to the control conductor C1080 of the trunk line 1080 and completes, at RA1021 and RC1022, an obvious path for applying ground potential to the control conductor C1080, thereby to mark the trunk circuit 1000 as busy to the toll switch train in order to prevent seizure thereof by the toll switch train.

Continuing now with the operation of the trunk circuit 1000 incident to the seizure of the trunk line 1080 by the toll selector switch 800, the relay R1030, upon operating, also prepares, at RA1030, a point in a circuit, traced hereinafter, for energizing the upper winding of the relay R1040. Also, it is noted that the application of ground potential to the control conductor C1087 of the trunk line 1084 extending to the combined local and toll connector switch 1090, causes the last-mentioned switch to operate and become responsive to impulses transmitted thereto. Also, it is noted that the wiper 802 of the wiper set of the mechanism 801 is now connected by way of the line conductor C1081 of the trunk line 1080, RA1044, RC1043, RC1072 and RA1071 to the line conductor C1085 of the trunk line 1084; and the wiper 803 of the wiper set of the mechanism 801 is connected by way of the line conductor C1082, RA1046, RC1045, RC1075 and RA1074 to the line conductor C1086 of the trunk line 1084. When the combined local and toll connector switch 1090 operates, as previously explained, a loop circuit is completed therein between the line conductors C1085 and C1086 of the trunk line 1084 over which subsequent impulses transmitted from the sender control circuit 300 are conducted.

Also, upon operating, the electropolarized relay R810 in the toll selector switch 800 renders the sender control circuit 300 operative to transmit the second and third digits mentioned over the cable 786, the toll selector switch 800, and the trunk circuit 1000 to the combined local and toll connector switch 1090, thereby to cause the last-mentioned switch to operate and seize the trunk line 1510 extending to the paystation line circuit 1500 individually associated with the paystation line 1501. The subsequent operation of the combined local and toll connector switch 1090 depends upon the idle or busy condition of the

paystation line 1501, as will be explained more fully hereinafter. After all of the digits have been transmitted by the sender control circuit 300 to the combined local and toll connector switch 1090, the sender control circuit 300 operates to cause ground potential to be applied to the conductor C191 in the cable 786, thereby to complete the previously traced circuit for energizing the upper winding of the cut-through relay R760 in the finder switch 700, as previously explained. The sender control circuit 300 is then automatically released as previously noted.

The cut-through relay R760 in the finder switch 700 then operates to complete, at RA1765, the previously traced holding circuit for energizing the lower winding thereof, to complete, at RA1764, the previously traced holding circuit for energizing the upper winding of the electropolarized relay R810 in the toll selector switch 800, and to complete, at RA1763, a circuit for energizing the upper winding of the relay R1040 in the trunk circuit 1000 in series with the winding of the relay R1120 in the relay group 1200A. The last-mentioned circuit extends from ground at the upper winding of R1040, by way of the winding of R1040, RC1048, RA1048, RA1030, the control conductor C1083 of the trunk line 1080, the wiper 804 of the wiper set of the mechanism 801, RA871, the control conductor C1789 of the trunk line 793, RA1763, the supervisory lamp L776, the contact 774 of the talk key 780 of the finder switch 700, the conductor C1284 in the cable 1286, RA1217, RC1219, C1185, the resistor 1122, and the winding of R1120 to battery. When energized over the above-traced circuit, the relay R1120 operates to complete, at RA1121, the previously mentioned path for short-circuiting the resistor 1122, thereby to reduce the series resistance of the above-traced circuit, whereupon the relay R1040 in the trunk circuit 1000 operates. Upon operating the relay R1040 interrupts, at RA1048 and RC1048, a point in the previously traced circuit for energizing the upper winding thereof in series with the winding of the relay R1120 and completes, at RA1048 and RC1049, an alternative path for applying ground potential to the control conductor C1083 of the trunk line 1080, thereby to retain the relay R1120 in its operated position. The last-mentioned path extends from ground at RA1051 by way of RC1049, RA1048 and RA1030 to the control conductor C1083. Also, upon operating, the relay R1040 completes, at RA1040, a holding circuit for energizing the lower winding thereof, this circuit extending from the grounded control conductor C1089 of the trunk line 1080 by way of RA1021, RC1023, RA1040 and the lower winding of R1040 to battery. At this time the supervisory lamp L776 is illuminated, thereby to indicate to the operator at the first operator position that the sender control circuit 300 has operated to transmit the digits to the combined local and toll connector switch 1090. Also, upon operating, the cut-through relay R760 in the finder switch 700 completes, at RA1761 and RA1762, the previously traced connection between the trunk circuit at the first operator position and the toll selector switch 800, the toll selector switch 800 being connected by way of the trunk line 1080 to the trunk circuit 1000 and the last-mentioned trunk circuit being connected by way of the trunk line 1084 to the combined local and toll connector switch 1090 at this time.

Also, upon operating, the relay R1040 in the trunk circuit 1000 interrupts, at RA1044 and 75

RC1043 and at RA1046 and RC1045, the previously traced metallic connection between the line conductors C1081 and C1082 of the trunk line 1080 and the line conductors C1085 and 5 C1086 of the trunk line 1084 and completes, at RA1042 and RA1044 and at RA1045 and RA1046, a connection between the trunk line 1080 and the repeater 1010. More specifically, the line conductor C1081 of the trunk line 1080 is connected by way of RA1044, RA1042, the winding 1012, the condenser 1016, the winding 1014, RA1045 and RA1046 to the line conductor C1082 of the trunk line 1080. Also, the relay R1040 completes, at RA1041 and at RA1047, a connection between the trunk line 1084 and the repeater 1010. More specifically, the line conductor C1085 of the trunk line 1084 is connected by way of RA1071, RC1072, RA1041, the winding 1011, the condenser 1015, the winding 1013, RA1047 10 RC1075 and RA1074 to the line conductor C1086 of the trunk line 1084. Also, it is noted that the windings of the relay R1050 are connected across the condenser 1015, one terminal of the condenser 1015 being connected by way of the upper winding 20 of R1050 to ground, and the other terminal of the condenser 1015 being connected by way of the lower winding of R1050 to battery.

When the combined local and toll connector switch 1090 operates to seize the trunk line 1510 extending to the paystation line circuit 1500, the idle or busy condition of the paystation line circuit 1500 is first tested. In the event the paystation line 1501 is busy at this time, ground potential appears upon the control conductor C1512 of the trunk line 1510, this ground potential being derived at RC1524 and extending therefrom by way of RA1523 to the control conductor C1512 of the trunk line 1510. This application of ground potential to the control conductor C1512 of the trunk line 1510 causes the combined local and toll connector switch 1090 to operate and return busy tone current over the trunk line 1084 to the repeater 1010, which repeater repeats the busy tone current to the trunk circuit at the first operator position by way of the finder-selector link illustrated, in an obvious manner, thereby to cause the receiver of the telephone instrument thereat to produce busy tone. The operator at the first operator position 45 then advises the calling party that the desired connection cannot be had due to the busy condition of the paystation line 1501. The operator at the first operator position then releases the front end of the connection and subsequently 50 sets up the connection again or advises the calling party to abandon the call.

Assuming that the paystation line 1501 is idle, when the combined local and toll connector switch 1090 seizes the trunk line 1510 extending 55 to the paystation line circuit 1500 individually associated with the paystation line 1501, battery potential appears upon the control conductor C1512 of the trunk line 1510, thereby to cause the combined local and toll connector switch 1090 to operate and cause ground potential to be applied to the control conductor C1512 of the trunk line 1510. This application of ground potential to the control conductor C1512 of the trunk line 1510 completes a circuit for energizing the relay 60 R1540, this circuit extending from the grounded control conductor C1512 by way of RA1523, RC1525, RA1534, RC1535 and the lower winding of R1540 to battery. When energized over the above-traced circuit, the relay R1540 operates to 65 interrupt, at RA1541 and RC1542 and at RA1545

and RC1547, points in the previously traced circuit for energizing the upper winding of the relay R1520.

The operator at the first operator position 1400 then causes ringing current to be projected over 5 the paystation line 1501, this being accomplished by operating the ring key K5 at the first operator position to its front position. When the ring key K5 is operated to its front position, the previously traced circuit for energizing the front 10 split relay R1210 is completed at the contact 1405 thereof, and the previously traced path for connecting alternating ringing current to the conductor C1468 is completed at the contact 1406 thereof. The front split relay R1210 operates, 15 as previously explained, thereby to disconnect the conductors C1277 and C1278 included in the cable 1286 from the trunk circuit at the first operator position and to connect the last-mentioned conductors to the conductors C1469 20 and C1468, as previously explained. When the conductor C1278 is connected to the conductor C1468 having alternating ringing current connected thereto, a circuit is completed for energizing the relay R1060 in the trunk circuit 1000, 25 the last-mentioned circuit extending from the ungrounded terminal of the grounded source of alternating ringing current by way of the contact 1406 of the ring key K5, C1468, RC1213, RA1211, the conductor C1278 in the cable 1286, 30 RA1754, RA1762, the conductor C788 of the trunk line 793, RA813, RC814, RA893, the wiper 803 of the wiper set of the mechanism 801, the line conductor C1082 of the trunk line 1080, RA1046, RA1045, the winding 1014, the condenser 1052, 35 the winding of R1060, and RA1077 to ground. When energized over the above-traced circuit, the relay R1060 operates to interrupt, at RA1061, a point in a circuit, traced hereinafter, for energizing the winding of the relay R1070 and to interrupt, at RA1062, a point in the previously 40 traced path for applying ground potential to the control conductor C1087 of the trunk line 1084 extending to the combined local and toll connector switch 1090. When ground potential is 45 removed from the control conductor C1087 of the trunk line 1084, the combined local and toll connector switch 1090 operates to cause ringing current to be projected over the line conductors C1511 and C1513 of the trunk line 1510 to the 50 paystation line circuit 1500 and therefrom by way of the line conductors C1502 and C1503 of the paystation line 1501 to the paystation T2, whereupon the ringer at the paystation T2 operates in order to indicate to the called party thereat that 55 a call is extended thereto.

When the call is answered at the paystation T2, the combined local and toll connector switch 1090 switches through, thereby to complete a loop circuit between the paystation T2 and the combined local and toll connector switch 1090 and to complete a circuit for energizing in series the upper and lower windings of the relay R1050 in the trunk circuit 1000. When the last-mentioned circuit is completed, the relay R1050 operates to 60 interrupt, at RA1051, a point in the previously traced path for applying ground potential to the control conductor C1083 of the trunk line 1080, thereby to interrupt the previously traced circuit for illuminating the supervisory lamp L776. 65 When the supervisory lamp L776 is extinguished, the operator at the first operator position 1400 is advised that the called party at the paystation T2 has answered the call extended thereto and she then operates the ring key K5 back to its 70 75

normal position. When the ring key K5 is operated back to its normal position, the previously traced circuit for energizing the front split relay R1210 is interrupted, at the contact 1405 thereof, thereby to cause the latter relay to restore; and the previously traced circuit for energizing the relay R1060 in the trunk circuit 1000 is interrupted, at the contact 1406 thereof, thereby to cause the latter relay to restore. Upon restoring, the relay R1060 recompletes, at RA1062, the previously traced path for applying ground potential to the control conductor C1081 of the trunk line 1084, thereby to cause the combined local and toll connector switch 1090 to operate and interrupt the projection of ringing current over the paystation line 1501. Also, upon restoring, the relay R1060 prepares, at RA1061, a point in the previously mentioned circuit for energizing the winding of the relay R1070. When the front split relay R1210 in the relay group 1200A restores, the telephone instrument at this position is operatively connected with the paystation T2 by way of the finder-selector link illustrated, the trunk circuit 1000, the paystation line circuit 1500, and the paystation line 1501.

The present call routed to the paystation T2 may be paid for by the called party thereat. In this event, the operator at the first operator position then advises the called party at the paystation T2 to insert certain coins in the coin slot of the instrument thereat in the usual manner. In order to collect the coins at the paystation T2, the operator at the first operator position 1400 operates the coin collect key K2 at her position to its front position. When the coin collect key K2 is operated to its front position, an obvious circuit is completed, at the contact 1418 thereof, for energizing the winding of the front split relay R1210, and an obvious path is completed, at the contact 1419 thereof, for applying ground potential to the conductor C1468. When thus energized, the front split relay R1210 operates, as previously explained, thereby to complete a connection between the conductors C1468 and C1469 and the conductors C1278 and C1277, respectively, in the cable 1286. This application of ground potential to the conductor C1468 completes a path for short-circuiting the winding of the relay R1060 in the trunk circuit 1000. The last-mentioned path extends from ground at RA1077 by way of the winding of R1060, the condenser 1052, the winding 1014, RA1045 and RA1046 to the line conductor C1082 of the trunk line 1080, the line conductor C1082 of the trunk line 1080 being connected by way of the previously traced circuit including the toll selector switch 800 to the grounded conductor C1468. This short-circuiting of the winding of the relay R1060 in the trunk circuit 1000 positively prevents operation thereof at this time. Also, at the contact 1420 of the coin collect key K2, an obvious circuit is completed for connecting the positive terminal of a 110 volt D. C. source of supply to the conductor C1469. This application of positive potential to the conductor C1469 completes, by way of the previously traced circuit including the toll selector switch 800 extending to the line conductor C1081 of the trunk line 1080, a connection for applying positive potential to the last-mentioned line conductor. This application of positive potential to the line conductor C1081 of the trunk line 1080 completes a circuit for energizing the winding of the relay R1070, the last-mentioned circuit extending from ground potential at the winding of R1070, by way of the winding of R1070, RA1061, the winding 1012, RA1042 and RA1044 to the line conductor C1081 having positive potential thereon. Shortly after being energized over the above-traced circuit, the relay R1070, being of the slow-to-operate type, operates to interrupt, at RA1077, a point in the previously traced circuit for energizing the winding of the relay R1060, thereby to positively prevent operation of the last-mentioned relay at this time. Also, upon operating, the relay R1070 interrupts, at RA1071 and RC1072 and at RA1074 and RC1075, the previously traced connection between the line conductors C1085 and C1086 of the trunk line 1084 extending to the combined local and toll connector switch 1090 and the repeater 1010 and completes, at RA1071 and RC1073 and at RA1074 and RC1076, a connection between the line conductors C1085 and C1086 of the trunk line 1084 and the line conductor C1081 of the trunk line 1080. The last-mentioned connection extends from the line conductor C1085 of the trunk line 1084 by way of RA1071 to RC1073, and from the line conductor C1086 of the trunk line 1084 by way of RA1074 and RC1076 to RC1073, and from RC1073 by way of RA1042 and RA1044 to the line conductor C1081 of the trunk line 1080. At this time the positive potential appearing upon the line conductor C1081 of the trunk line 1080 is projected by way of the previously traced circuit including the line conductors C1085 and C1086 of the trunk line 1084, the combined local and toll connector switch 1090, the line conductors C1511 and C1513 of the trunk line 1510, and the line conductors C1502 and C1503 of the paystation line 1501 to the paystation T2. This positive potential projected over the line conductors of the paystation line 1501 to the paystation T2 causes the coin collecting apparatus thereat to operate and collect the coin disposed in the coin slot of the instrument thereat in the usual manner.

After operating the coin collect key K2 to its front position, the operator at the first operator position 1400 returns the last-mentioned key to its normal position. When the coin collect key K2 is returned to its normal position, the previously mentioned circuit for energizing the front split relay R1210 is interrupted at the contact 1418 thereof; the previously mentioned path for applying ground potential to the control conductor C1468 is interrupted at the contact 1419 thereof; and the previously mentioned path for connecting the positive terminal of the 110 volt D. C. source of supply to the conductor C1469 is interrupted at the contact 1420 thereof, thereby to cause the front split relay R1210 in the relay group 1200A and the relay R1070 in the trunk circuit 1000 to restore shortly thereafter, both of the last-mentioned relays being of the slow-to-release type. It is noted that the relay R1070 in the trunk circuit 1000 is of the slow-to-release type, thereby to permit the coin control apparatus at the pay-station T2 to completely operate before the latter relay restores. Upon restoring, the relay R1070 interrupts, at RA1071 and RC1073 and at RA1074 and RC1076, the previously traced connection between the line conductors C1085 and C1086 of the trunk line 1084 and the line conductor C1081 of the trunk line 1080 and completes, at RA1071 and RC1072 and at RA1074 and RC1075, the previously traced connection between the line conductors C1085 and C1086 of the trunk line 1084 and the repeater 1010. It is noted that when the line conductors of the trunk line 1084 are disconnected from the repeater 1010, the relay R1050 restores; and when

- the line conductors of the trunk line 1084 are reconnected to the repeater 1010, the relay R1050 reoperates. When the relay R1050 restores, it completes, at RA1051, the previously traced path 5 for applying ground potential to the control conductor C1083 of the trunk line 1080, thereby to complete the previously traced circuit for illuminating the supervisory lamp L176; and when the relay R1050 reoperates, it interrupts, at RA1051, the previously traced circuit for illuminating the supervisory lamp L176. Accordingly, at this time, when the supervisory lamp L176 is illuminated, the operator at the first operator position is advised that the coin control apparatus 10 at the paystation T2 is being controlled; and when the supervisory lamp L176 is extinguished, the operator at the first operator position is advised that the connection is reestablished to the paystation T2.
- Instead of collecting the coin at the paystation T2, as explained above, the operator at the first operator position 1400 may wish to return the coin disposed in the coin slot of the instrument at the paystation T2 to the called party thereat. 20 This is accomplished by operating the coin return key K1 at the first operator position to its front position. When the coin return key K1 is operated to its front position, an obvious circuit is completed, at the contact 1411 thereof, for energizing the front split relay R1210, thereby to cause the latter relay to operate. Also, when the coin return key K1 is operated to its front position, an obvious path is completed, at the contact 1412 thereof, for applying ground potential to the conductor C1468. Upon operating, the front split relay R1210 disconnects the conductor C1271 and conductor C1278 in the cable 1286 from the trunk circuit at the first operator position and connects the last-mentioned conductors to the conductors C1468 and C1469, as previously explained. When the conductor C1278 is connected to the conductor C1468, the previously traced path for short-circuiting the winding of the relay R1060 in the trunk circuit 1000 is completed, thereby to prevent operation of the last-mentioned relay at this time. Finally, when the coin return key K1 is operated to its front position, a path is completed, at the contact 1413 thereof, for connecting the negative terminal of the 110 volt D. C. source of supply to the conductor C1469, thereby to complete the previously traced path for applying negative potential to the line conductor C1081 of the trunk line 1080 and the previously traced circuit for energizing the winding of the relay R1070 in the trunk circuit 1000, thereby to cause the latter relay to operate, as previously explained. Upon operating, the relay R1070 completes, at RA1071 and RC1073 and at RA1074 and RC1076, the previously traced connection between the line conductors C1085 and C1086 of the trunk line 1084 and the line conductor C1081 of the trunk line 1080, thereby to cause current to be projected by way of the line conductors C1085 and C1086 of the trunk line 1084, the combined local and toll connector switch 1090, and the line conductors C1511 and C1513 of the trunk line 1510 extending to the paystation line circuit 1500 over the line conductors C1502 and C1503 of the paystation line 1501. This current projected over the line conductors of the paystation line 1501 causes the coin control apparatus at the paystation T2 to operate and refund the coin deposited in the coin slot of the instrument thereat to the subscriber, as previously explained.
- After operating the coin return key K1 to its front position, the operator at the first operator position returns the last-mentioned key to its normal position, thereby to interrupt, at the contact 1411 thereof, the previously mentioned circuit for energizing the winding of the front split relay R1210 in order to cause the latter relay to restore and to interrupt, at the contact 1412 thereof, the previously traced path for short-circuiting the winding of the relay R1060 in the trunk circuit 1000. Finally, when the coin return key K1 is operated to its normal position, the previously traced path for connecting the negative terminal of the 110 volt D. C. source of supply to the conductor C1469, at the contact 1413 thereof, is interrupted in order to cause the relay R1070 in the trunk circuit 1000 to restore, as previously explained. After the front split relay R1210 in the relay group 1200A and the relay R1070 in the trunk circuit 1000 restore, the telephone instrument at the first operator position is 20 operatively connected to the telephone instrument at the paystation T2, as previously explained.
- Also, it is noted that the called party at the paystation T2 has switchhook supervision and may signal the operator at the first operator position by repeatedly operating the switchhook at the paystation T2. Each time the switchhook at the paystation T2 is depressed, the combined local and toll connector switch 1090 is controlled to 30 cause the relay R1050 in the trunk circuit 1000 to restore; and each time the switchhook at the paystation T2 is released, the last-mentioned connector switch operates to cause the relay R1050 to reoperate. The operation of the relay R1050 35 controls the previously traced circuit for illuminating the supervisory lamp L176 regardless of the position of the talk key 780 of the finder switch 700, as previously explained.
- The supervision and the release of the established connection routed by way of the finder-selector link illustrated are accomplished in the manner previously explained. It is noted that when the established connection is released, the toll selector switch 800 is returned to its normal 40 position, whereupon the previously traced path for applying ground potential to the control conductor C1080 of the trunk line 1080 is interrupted. When ground potential is removed from the control conductor C1080 of the trunk line 1080, the 45 previously traced circuits for energizing the winding of the relay R1030 and the lower winding of the relay R1040 are interrupted, thereby to cause the latter relays to restore. Upon restoring, the relay R1040 disconnects the line conductors of the trunk line 1080 from the repeater 1010, disconnects the line conductors of the trunk line 1084 from the repeater 1010, and reconnects the line conductors of the trunk line 1080 to the line conductors of the trunk line 1084, as previously 50 explained. When the relay R1030 restores, it interrupts, at RA1031, the previously traced path for applying ground potential to the control conductor C1087 of the trunk line 1084, thereby to cause the combined local and toll connector 55 switch 1090 to restore to its normal position. At this time the trunk circuit 1000 is completely released. Also, the trunk circuit 1000 is marked as idle to the switches having access thereto by the presence of battery potential, at the winding of the relay R1030, upon the control conductor C1080 of the trunk line 1080.
- When the combined local and toll connector switch 1090 is released, the previously mentioned path for applying ground potential to the control 60

conductor C1512 of the trunk line 1510 is interrupted, thereby to interrupt the previously traced circuit for energizing the lower winding of the relay R1540, whereupon the latter relay restores to prepare, at RA1541 and RC1542 and at RA1545 and RC1547, points in the previously traced circuit for energizing the upper winding of the relay R1520 in the paystation line circuit 1500. At this time the paystation line circuit 1500 is completely released, this line circuit being marked as idle to the switches having access thereto by the presence of battery potential, at the lower winding of the relay R1540, upon the control conductor C1512 of the trunk line 1510.

15 *Extension of a call from the switchboard to the C. A. X. network*

Assuming that an incoming call answered at one of the operator positions at the switchboard, such, for example, as the first operator position 1400, is to be extended to a subscriber substation included in the C. A. X. network, such, for example as the subscriber substation T3 in the tandem exchange C, the operator at the first operator position initiates the extension of the call by actuating the sending key set 303 as previously noted. Assuming that the incoming call has been answered at the first operator position and routed thereto by way of the finder switch 700 of the finder-selector link illustrated and that the sender control circuit 300 is operatively associated with the cable 786 individually extending to the toll selector switch 800 and with the digit register and control circuit 304, the operator at the first operator position actuates the keys of the sending key set 303, thereby to cause the digit register and control circuit 304 to register a series of digits corresponding to the directory number of the subscriber substation T3 in the tandem exchange C.

It is noted that the call may be routed from the first operator position to the tandem exchange C by way of a particular C. A. X. trunk in the group of C. A. X. trunks extending between the central office A and the tandem exchange C or by way of any idle one of the C. A. X. trunks in the group of C. A. X. trunks extending between the central office A and the tandem exchange C; and that the call is then routed from the tandem exchange C to the subscriber substation T3 by way of the switch train in the tandem exchange C. In the event the call is to be routed from the first operator position 1400 to the tandem exchange C by way of an individual C. A. X. trunk in the group of C. A. X. trunks extending therebetween, such for example, as the C. A. X. trunk 510, the sending key set 303 is operated, thereby to cause the digit register and control circuit 304 to operate and register the directory number of the particular C. A. X. trunk 510, whereupon the toll selector switch 800 operates as a connector switch, in a manner more fully described subsequently, to seize the C. A. X. trunk 510. In the event a call is to be routed from the first operator position to the tandem exchange C by way of any idle C. A. X. trunk in the group of C. A. X. trunks extending therebetween, the sending key set 303 is operated, thereby to cause the digit register and control circuit 304 to operate and register the directory number of the first C. A. X. trunk in the group of C. A. X. trunks extending therebetween, whereupon the toll selector switch 800 operates as an automatic rotary and level hunting selector switch, in a manner more fully described subsequently, to hunt

for an idle C. A. X. trunk in the group of C. A. X. trunks extending between the central office A and the tandem exchange C.

In the present instance, assuming that the sending key set 303 is operated to register the directory number of the particular C. A. X. trunk 510 extending between the central office A and the tandem exchange C, the sender control circuit 300 then operates to transmit the impulses comprising the first digit by way of the line conductors C787 and C788 of the trunk line 793 to the toll selector switch 800, thereby to cause the line relay R820 in the toll selector switch 800 to operate intermittently, as previously explained. The operation of the line relay R820 causes the vertical magnet M801 to be operated a predetermined number of times corresponding to the number of impulses comprising the first digit, whereupon the wiper set of the mechanism 801 is driven a corresponding number of steps. It is noted that the group of trunk lines extending to the C. A. X. trunk circuits individually associated with the C. A. X. trunks extending between the central office A and the tandem exchange C are terminated in the main contact bank of the mechanism 801 in several levels therein, such, for example, as the fourth, fifth and sixth levels therein. Further, it is noted that the trunk line 680 extends to the C. A. X. trunk circuit 600 individually associated with the C. A. X. trunk 510 extending between the central office A and the tandem exchange C.

At the conclusion of the first digit, the wiper set of the mechanism 801 occupies a vertical position adjacent one of the levels in the main contact bank of the mechanism 801 wherein the trunk line 680 is terminated. At the conclusion of the first digit, the line relay R820, the hold relay R830 and the relay R840 occupy their operated positions; also, the intermediate winding 40 of the electropolarized relay R810 is energized, thereby rendering this relay exceedingly fast to operate when the upper winding thereof is energized, as previously explained. At the conclusion of the first digit, the line relay R820 reoperates, thereby to interrupt, at RA821, a point in the previously traced holding circuit for energizing the lower winding of the relay R840. Due to the fact that the previously traced circuit for energizing the upper winding of the relay R840 is interrupted at this time, the relay R840 restores shortly thereafter, this relay being of the slow-to-release type. Upon restoring, the relay R840 interrupts, at RA842, a further point in the holding circuit for energizing the lower winding thereof, interrupts, at RA843 and RC844, a point in the previously traced circuit for energizing the winding of the vertical magnet M801 of the mechanism 801, and prepares, at RA843 and RC845, a point in a circuit, traced herein-after, for energizing the relay R880 in series with the rotary magnet M802 of the mechanism 801.

When the impulses comprising the second digit are transmitted from the sender control circuit 300 to the toll selector switch 800, the line relay R820 thereof operates intermittently, as previously noted. Each time the relay R820 restores, it completes, at RA822 and RC 824, the previously mentioned circuit for energizing the winding of the relay R880 in series with the winding of the rotary magnet M802. The last-mentioned circuit extends from ground at RA818 by way of RA822, RC824, RA834, RC835, RC859, RA858, RA843, RC845, RA851', RC853', RC867, RA865,

RA854', RC856', the winding of R880, RA817 and the winding of M802 to battery. Each time the line relay R820 operates, it interrupts, at RA822 and RC823, the previously traced circuit for energizing the relay R880 in series with the rotary magnet M802 and completes, at RA822 and RC823, the previously traced circuit for energizing the hold relay R830. Due to the fact that the hold relay R830 and the relay R880 are of the slow-to-release type, these relays remain in their operated positions during impulsing.

Upon operating, the relay R880 interrupts, at RA883, a point in the previously traced circuit for energizing the lower winding of the relay R860, interrupts, at RA861 and RC862, a point in the previously traced path for applying ground potential to the wiper 805 of the wiper set of the mechanism 801, and prepares, at RA861 and RA863, a point in a circuit, traced hereinafter, for energizing the relay R870. Each time the previously traced circuit for energizing the relay R880 and the rotary magnet M802 in series is completed, the rotary magnet M802 operates, thereby to drive the wiper set of the mechanism 801 one step in the rotary direction. In the present instance, the second digit comprises a predetermined number of impulses, thereby to cause the rotary magnet M802 to be driven a predetermined number of steps in order to engage the contact set in the main contact bank of the mechanism 801 terminating the trunk line 680 extending to the C. A. X. trunk circuit 600. The subsequent operation of the toll selector switch 800 depends upon the idle or busy condition of the trunk line 680.

At this time, in the event the trunk line 680, extending to the C. A. X. trunk circuit 600 is busy, ground potential appears upon the control conductor C864 thereof, the path for applying ground potential to the control conductor C684 extending from ground at RC654 by way of RA654, RC647, RA645, RC646 and RA645 to the control conductor C684. This application of ground potential to the control conductor C684 of the trunk line 680 completes the previously mentioned circuit for energizing the winding of the relay R870, this circuit extending from the grounded control conductor C684 of the trunk line 680 by way of the wiper 805, RA881, RA883 and the winding of R870 to battery. When energized over the above-traced circuit, the relay R870 operates to prepare, at RA872, a point in a holding circuit for energizing the winding thereof and to interrupt, at RA871, a point in a path, traced hereinafter, for applying ground potential to the control conductor C789 of the trunk line 793. Also, upon operating, the relay R870 prepares, at RA873, a point in the previously traced circuit for energizing the lower winding of the relay R860.

Shortly following the conclusion of the second digit transmitted to the toll selector switch 800, the relay R880, being of the slow-to-release type, restores to complete, at RA883 and RC884, the previously mentioned holding circuit for energizing the winding of the relay R870, this circuit extending from ground at RA883 by way of C890, MA804, RA861, RC862, MA803, RA872, RC884, RA883 and the winding of R870 to battery. Also, upon restoring, the relay R880 completes, at RA885, the previously traced circuit for energizing the lower winding of the relay R860, thereby to cause the latter relay to operate. Upon operating, the relay R860 prepares, at RA864, the previously traced circuit for energizing the intermediate winding of the electropolarized relay

R810 in series with the upper winding of the relay R890 and interrupts, at RA861 and RC862, a point in the previously traced holding circuit for energizing the winding of the relay R870, thereby to cause the latter relay to restore shortly thereafter, the latter relay being of the slow-to-release type. Also, upon operating, the relay R860 completes, at RA861 and RA863, an alternative holding circuit for energizing the lower winding thereof, the last-mentioned circuit extending from ground at RA883, by way of C890, MA804, RA861, RC863, RA885 and the lower winding of R860 to battery.

When the relay R870 restores, it completes, at RA871, the previously traced circuit for energizing the intermediate winding of the electropolarized relay R810 in series with the upper winding of the relay R890, thereby to cause the electropolarized relay R810 and the relay R890 to operate. Upon operating, the electropolarized relay R810 completes, at RA816, the previously traced holding circuit for energizing the intermediate winding thereof and interrupts, at RA817, a point in the previously traced circuit for energizing the relay R880 in series with the rotary magnet M802. Also, upon operating, the electropolarized relay R810 interrupts, at RA818, a further point in the previously traced circuit for energizing the release magnet M805 of the mechanism 801 and completes, at RA816, a holding circuit for energizing the upper winding of the relay R890 in series with the lower winding of the relay R860, the last-mentioned circuit extending from the grounded control conductor C790 of the trunk line 793 by way of RA816, RA864, RA877, the upper winding of R890, C890, MA804, RA861, RC863, RA885 and the lower winding of R860 to battery. Finally, upon operating, the electropolarized relay R810 interrupts, at RA811 and RC811 and at RA813 and RC813, the previously traced circuit for energizing the line relay R820, thereby to cause the latter relay to restore. Upon restoring, the line relay R820 interrupts, at RA822 and RC823, a further point in the previously traced circuit for energizing the hold relay R830. Shortly thereafter the hold relay R830 restores to interrupt, at RA831, the previously traced path for connecting battery potential at the resistor 827 to the control conductor C789 of the trunk line 793, thereby to cause the sender control circuit 300 to operate and transmit the remainder of the digits to the toll selector switch 800. Upon operating, the relay R890 interrupts, at RA891 and at RA893, the connection between the line conductors C787 and C788 of the trunk line 793 and the wipers 802 and 803 of the wiper set of the mechanism 801, thereby to prevent the impulses comprising the remainder of the digits transmitted by the sender control circuit 300 from being transmitted over the seized busy trunk line 680. At this time the electropolarized relay R810 and the relays R860 and R890 in the toll selector switch 800 occupy their operated positions.

Also, upon operating, the relay R890 completes, at RA892, the previously traced path for applying interrupted ground potential from the conductor C809 to the control conductor C789 of the trunk line 793. When the sender control circuit 300 operates to transmit the remainder of the digits and at the conclusion thereof, it operates to cause ground potential to be applied to the conductor C791 in the cable 786, as previously explained, thereby to cause the cut-through relay R760 to operate. Upon operating, the cut-through relay R760 completes, at RA765, the previously traced

- holding circuit for energizing the lower winding thereof, completes, at RA764, the previously mentioned path for applying ground potential to the control conductor C790 of the trunk line 793, 5 thereby to hold the toll selector switch 800 in its operated position, as previously explained, and completes, at RA763, the previously traced circuit for energizing the relay R1120 in the relay group 1200A. The relay R1120 then operates intermittently, thereby to cause the supervisory lamp L776 to flash as previously explained. The flashing of the supervisory lamp L776 indicates to the operator at the first operator position that the C. A. X. trunk 510 extending between the central 10 office A and the tandem exchange C is busy. The operator at the first operator position then releases the connection between the finder switch 700 and the toll selector switch 800, thereby to cause the toll selector switch 800 to be released, 15 as previously explained.
- In the event the trunk line 680 extending to the C. A. X. trunk circuit 600 is idle, when the wiper set of the mechanism 801 engages the contact set in the main contact bank thereof terminating the trunk line 680 extending to the C. A. X. trunk circuit 600, battery potential appears upon the control conductor C684 of the trunk line 680 which is engaged by the wiper 805 of the wiper set of the mechanism 801. This 20 battery potential is derived in the C. A. X. trunk circuit 600 from the dial-out relay R620 therein and extends from battery at the dial-out relay R620 by way of the upper and lower windings thereof in multiple, RC655, RA654, RC647, RA645, 25 RC646 and RA645 to the control conductor C684 of the trunk line 680. This application of battery potential to the wiper 805 of the wiper set of the mechanism 801 completes a path for short-circuiting the winding of the relay R870, this path 30 extending from battery potential appearing upon the wiper 805 of the wiper set of the mechanism 801 by way of RA881, RA883 and the winding of R870 to battery. Accordingly, the relay R870 does not operate, and shortly following the 35 conclusion of the second digit transmitted to the toll selector switch 800, the relay R880 restores, as previously noted. Upon restoring, the relay R880 completes, at RA881 and RC882, the previously traced circuit for energizing the upper 40 winding of the electropolarized relay R810, thereby to cause the last-mentioned relay to operate. Upon operating, the electropolarized relay R810 completes, at RA816, the previously traced holding circuit for energizing the intermediate winding thereof, interrupts, at RA817, 45 the previously traced circuit for energizing the relay R880 in series with the rotary magnet M802, interrupts, at RA818, a point in the previously traced circuit for energizing the hold relay R830, and completes, at RA815, the previously traced path for applying ground potential to the wiper 805 of the wiper set of the mechanism 801. Also, the electropolarized relay R810 interrupts, at RA811 and RC811 and at RA813 and RC813, 50 the previously traced circuit for energizing the upper and lower windings of the line relay R820, thereby to cause the latter relay to restore, and completes, at RA811 and RC812 and at RA813 and RC814, the previously traced connection between the line conductors C787 and C788 of the trunk line 793 and the wipers 802 and 803 of the wiper set of the mechanism 801. Immediately 55 the electropolarized relay R810 operates, the line relay R820 restores and shortly thereafter the hold relay R830 restores. Upon restoring, the

hold relay R830 interrupts, at RA831, the previously traced path for applying battery potential at the resistor 827 to the control conductor C789 of the trunk line 793, thereby to render the sender control circuit 300 operative to transmit 5 additional digits to the toll selector switch 800.

At this time the wipers 802, 803, 804 and 805 of the wiper set of the mechanism 801 engage the contacts in the contact set in the main contact bank of the mechanism 801 respectively terminating the conductors C682, C681, C683 and C684, respectively, of the trunk line 680. The wipers 802 and 803 are operatively connected by way of the previously traced path in the toll selector switch 800 to the line conductors C787 and C788, 10 respectively, of the trunk line 793 extending to the sender control circuit 300. Also, no potential appears upon the wiper 804 of the wiper set of the mechanism 801 at this time, while ground potential appears upon the wiper 805 of the wiper 15 set of the mechanism 801. This application of ground potential to the wiper 805 of the wiper set of the mechanism 801 completes a circuit for energizing in multiple the upper and lower windings of the dial-out relay R620 in the C. A. X. 20 trunk circuit 600, this circuit extending from the grounded wiper 805 by way of the control conductor C684 of the trunk line 680, RA615, RC616, RA645, RC647 and RA654 to RC655; from C655 by way of the lower winding of R620 to battery; 25 and from RC655 by way of RA629 and the upper winding of R620 to battery. When energized over the above-traced circuit, the dial-out relay R620 operates to interrupt, at RA629, a point in the previously traced circuit for energizing the 30 upper winding thereof, this relay remaining in its operated condition at this time due to the completed circuit for energizing the lower winding thereof. Also, upon operating, the dial-out relay R620 interrupts, at RA620, a further point 35 in the previously traced circuit for energizing the start relay R640, thereby to prevent operation of the last-mentioned relay at this time. Also, the relay R620 interrupts, at RA622 and RC623 and at RA627 and RC628, a connection between 40 the line conductors C681 and C682 of the trunk line 680 and the repeater 633, the line conductor C681 being normally connected by way of RA622, RC623, the winding 637, the condenser 638, the winding 639, RC628 and RA627 to the line conductor C682. Finally, the dial-out relay R620 45 completes, at RA621 and RC622, at RA623 and RA624, and at RA626 and RA627, a path for applying battery potential at the resistor 632 to the control conductor C636. The last-mentioned 50 path extends from battery at the resistor 632, by way of the resistor 632, RA626, RA627, the line conductor C682 of the trunk line 680, the wiper 802 of the wiper set of the mechanism 801, RA891, RA860, RC812, RA811 to the line conductor C787 of the trunk line 793, and from the line conductor C788 of the trunk line 793 by way of RA813, RC814, RA893, the wiper 803 of the wiper set of the mechanism 801, the line conductor C681 of the trunk line 680, RA622, RA621, 55 RA623 and RA624 to the control conductor C636. Further, it is noted that the line conductors C787 and C788 of the trunk line 793 are operatively connected by way of the cable 786 to the sender control circuit 300, apparatus being provided in 60 the sender control circuit 300 for intermittently connecting the line conductors C787 and C788 of the trunk line 793 together, thereby to cause the battery impulses to be transmitted by way of the 65 previously traced circuit to the control conductor 70 75

C636. The application of battery potential to the control conductor C636 completes the previously traced path comprising the simplex link including the C. A. X. trunk 510 for applying battery potential to the control conductor C515 extending between the neutral point between the windings 613 and 614 connected across the line conductors C511 and C512 of the C. A. X. trunk 510 and the dual call control circuit and repeater 500. This application of battery potential to the control conductor C515 causes the dual call control circuit and repeater 500 to operate. More particularly, the dual call control circuit and repeater 500 operatively connects together the trunk lines 501 and 504 extending thereto and causes the selector switch 516 to be operative in response to impulses transmitted thereto. At this time the selector switch 516 is operatively connected by way of the trunk line 501 and the dual call control circuit and repeater 500 to the trunk line 504, the line conductors C505 and C506 of the trunk line 504 being operatively connected by the condensers 507 and 508, respectively, to the line conductors C511 and C512 of the C. A. X. trunk 510, while the last-mentioned line conductors of the C. A. X. trunk 510 are operatively connected to the repeater 633 in the dual call trunk circuit 600.

The sender control circuit 300 then operates, as previously explained, thereby to interrupt the previously traced path for applying battery potential to the control conductor C636 in order to cause the series of impulses comprising the digits to be transmitted thereover, these impulses being transmitted by way of the previously traced connections to the selector switch 516. The selector switch 516 operates in response to the impulses comprising the first digit transmitted thereto, thereby to select a group of trunk lines extending to the connector switches having access to the subscriber substation T3 in the usual manner. The selector switch 516 then operates automatically in order to seize a trunk line extending to an idle connector switch in the previously selected group, such, for example, as the trunk line 530 extending to the connector switch 519, in the usual manner. When the trunk line 530 is seized by the selector switch 516, the connector switch 519 operates in order operatively to associate the selector switch 516 and the connector switch 519, whereupon the connector switch 519 is operative in response to digits transmitted thereto in the usual manner. The sender control circuit 300 continues to operate, thereby to transmit two additional digits by way of the previously traced connections to the dual call control circuit and repeater 500, thereby to cause the two digits to be transmitted by way of the trunk line 501, the selector switch 516 and the trunk line 530 to the connector switch 519. The connector switch 519 operates in response to the two digits transmitted thereto in order to seize the subscriber line 533 extending to the subscriber substation T3 in the usual manner. The subsequent operation of the connector switch 519 depends upon the idle or busy condition of the subscriber line 533 in accordance with the usual practice.

When the entire series of digits has been transmitted by the sender control circuit 300, the sender control circuit 300 operates to cause ground potential to be applied to the conductor C791 in the cable 786, as previously explained, thereby to cause the cut-through relay R760 to operate. Upon operating, the cut-through relay R760 completes, at RA765, the previously traced

holding circuit for energizing the lower winding thereof, completes, at RA764, the previously traced path for applying ground potential to the control conductor C790 of the trunk line 793, thereby to retain the toll selector switch 800 in its operated position, as previously explained, and completes, at RA761 and RA763, the previously traced connection between the trunk circuit at the first operator position 1400 and the wipers 802 and 803 of the wiper set of the mechanism 801. Also, the cut-through relay R760 completes, at RA763, the previously traced path for applying battery potential at the winding of the relay R1120 in the relay group 1200A to the control conductor C789 of the trunk line 793, thereby to cause battery potential to be applied to the wiper 804 of the wiper set of the mechanism 801. This application of battery potential to the wiper 804 completes a circuit for energizing the upper winding of the relay R610 in the C. A. X. trunk circuit 600, this circuit extending from battery potential appearing upon the wiper 804 by way of the control conductor C683 of the trunk line 680, RA613, RC612 and the winding of R610 to ground. When energized over the above-traced circuit, the relay R610 operates to complete, at RA614 and RA615, a holding circuit for energizing the lower winding thereof, this circuit extending from ground potential appearing upon the wiper 805 of the wiper set of the mechanism 801 by way of the control conductor C684 of the trunk line 680, RA615, RC614 and the lower winding of R610 to battery. Also, the relay R610 interrupts, at RA615 and RC616, the previously traced circuit for energizing the dial-out relay R620, thereby to cause the latter relay to restore. Furthermore, the relay R610 interrupts, at RA613 and RC612, a point in the previously traced circuit for energizing the upper winding thereof, prepares, at RA611 and RC613, a path for applying ground potential to the control conductor C683 of the trunk line 680, interrupts, at RA617, a further point in the previously traced circuit for energizing the start relay R640, and prepares, at RA610 and RC619, a point in a path, traced hereinafter, for applying battery potential at the resistor 685 to the control conductor C636.

Upon restoring, the dial-out relay R620 interrupts, at RA621 and RA622, at RA623 and RA624, and at RA626 and RA627, points in the previously traced path for applying battery potential at the resistor 632 to the control conductor C636 and completes, at RA622 and RC623 and at RA627 and RC628, the previously traced operative connection between the line conductors C681 and C682 of the trunk line 680 and the repeater 633. Also, upon restoring, the dial-out relay R620 completes, at RA624 and RC625, the previously mentioned circuit for applying battery potential at the resistor 685 to the control conductor C636, the last-mentioned path extending from battery at the resistor 685, by way of the resistor 685, RC619, RA610, the winding of R630, RC625 and RA624 to the control conductor C636.

At this time the connector switch 519 has seized the subscriber line 533 and is operatively connected by way of the trunk line 530 to the selector switch 516. Furthermore, the selector switch 516 is operatively connected by way of the trunk line 501, the dual call control circuit and repeater 500, the trunk line 504 and the C. A. X. trunk 510 to the repeater 633 in the C. A. X. trunk circuit 600. Furthermore, the trunk circuit at the first operator position 1400 is connected by way of the finder-selector link illustrated, the 75

trunk line 680 and the C. A. X. trunk circuit 600 to the repeater 633, as previously explained. When the entire series of digits has been transmitted to the dual call trunk circuit and repeater 500, the dual call control circuit and repeater 500 operates to apply ground potential to the control conductor C515, thereby to cause ground potential to be applied by way of the simplex link including the C. A. X. trunk 510 to the control conductor C636. This application of ground potential to the control conductor C636 completes the previously traced circuit for energizing the relay R630, thereby to cause the latter relay to operate. Upon operating, the relay R630 completes, at RA631, the previously mentioned path for applying ground potential to the control conductor C683 of the trunk line 680, this path extending from ground at RA631 by way of RA611 and RA613 to the control conductor C683. This application of ground potential to the control conductor C683 completes the previously traced path including the toll selector switch 800 for applying ground potential to the control conductor C789 of the trunk line 793, thereby to cause the relay R1120 in the relay group 1200A to operate, as previously explained, whereupon the supervisory lamp L776 is illuminated. The illumination of the supervisory lamp L776 indicates to the operator at the first operator position that the apparatus in the C. A. X. network has operated to seize the called subscriber line. In the event the called subscriber line 533 is busy, the connector switch 519 operates to cause busy tone current to be returned by way of the trunk line 530, the selector switch 516 and the trunk line 501 to the dual call control circuit and repeater 500, this busy tone current being repeated by the dual call control circuit and repeater 500 over the previously traced connection including the C. A. X. trunk 510 to the repeater 633 in the C. A. X. trunk circuit 600 and from the last-mentioned repeater by way of the previously traced connection to the talking repeater 1106 at the first operator position, thereby to indicate to the operator at the first operator position that the called subscriber line 533 terminating in the tandem exchange C is busy at this time. The operator at the first operator position then advises the calling party that the desired connection cannot immediately be had due to the busy condition of the called subscriber substation T3.

In the event the calling subscriber line 533 is idle at this time, the connector switch 519 operates in order to cause ringing current to be projected over the subscriber line 533 in the usual manner to the substation T3, a portion of this ringing current being returned over the previously traced connections to the talking repeater 1106 at the first operator position, thereby to indicate to the operator thereat that ringing current is being projected over the called subscriber line 533 to the substation T3.

When the subscriber at the called subscriber substation T3 answers the call, the connector switch 519 operates, thereby to complete an operative connection between the telephone instrument at the subscriber substation T3 and the dual call control circuit and repeater 500, the dual call control circuit and repeater 500 being operatively connected by way of the previously traced connections to the talking repeater 1106 at the first operator position. Also, the dual call control circuit and repeater 500 operates, thereby to cause battery potential to be applied to the

control conductor C515. This application of battery potential to the control conductor C515 causes battery potential to be applied by way of the simplex link including the C. A. X. trunk 510 to the control conductor C636. This application of battery potential to the control conductor C636 completes a path for short-circuiting the winding of the relay R630, thereby to cause the latter relay to restore. Upon restoring, the relay R630 interrupts, at RA631, a point in the previously traced path for applying ground potential to the control conductor C683 of the trunk line 680, thereby to interrupt the previously traced circuit for energizing the relay R1120 in the relay group 1200A and for illuminating the supervisory lamp L776. When the supervisory lamp L776 is extinguished, the operator at the first operator position is advised that the party at the called substation T3 in the C. A. X. network has answered the call extending thereto. The operator at the first operator position then communicates with the subscriber at the called substation T3 in the usual manner. Subsequently, the operator advises the calling party that the called party has answered and that the conversation may proceed.

It is noted that the subscriber at the called substation T3 has switchhook supervision and may signal the operator at the first operator position regardless of the position of the talk key 780 of the finder switch 700 by operating the switchhook of the telephone instrument at the subscriber substation T3. Each time the switchhook is depressed, the dual call control circuit and repeater is caused to operate, thereby to apply ground potential to the control conductor C515, this application of ground potential to the control conductor C515 being effective to complete the previously traced circuit for energizing the relay R630 in the C. A. X. trunk circuit 600. Conversely, each time the switchhook of the telephone instrument at the subscriber substation T3 is released, the dual call control circuit and repeater 500 is caused to operate to apply battery potential to the control conductor C515, this application of ground potential to the control conductor C515 being effective to short-circuit the winding of the relay R630 in the dual call trunk circuit 600. Accordingly, the relay R630 intermittently operates, thereby to complete intermittently, at RA631, the previously traced path for applying ground potential to the control conductor C683 of the trunk line 680 in order to cause ground potential to be intermittently applied to the control conductor C789 of the trunk line 793. In the event the talk key 780 of the finder switch 700 occupies its normal position, the application of ground potential to the control conductor C789 of the trunk line 793 completes the previously traced circuit extending by way of the contact 775 of the talk key 780 for illuminating the supervisory lamp L776; and in the event the talk key 780 occupies its operated position, the application of ground potential to the control conductor C789 of the trunk line 793 completes the previously traced circuit for energizing the relay R1120 in the relay group 1200A, thereby to cause the latter relay to operate and complete the previously traced circuit for illuminating the supervisory lamp L776. Accordingly, the supervisory lamp L776 is flashed, thereby to indicate to the operator at the first operator position that the subscriber at the called subscriber substation T3 in the tandem exchange C wishes her attention. The operator at the first operator

position then establishes the previously traced connection between the trunk circuit at her position and the finder-selector link illustrated, thereby to complete a connection in order to converse with the called party at the subscriber substation T3.

Assuming that the call from the first operator position 1400 at the switchboard in the central office A is to be routed to the tandem exchange C by way of the first idle C. A. X. trunk in the group of C. A. X. trunks extending therebetween, the operator at the first operator position operates the sending key set 303 to register the directory number of the first C. A. X. trunk in the group of C. A. X. trunks extending between the central office A and the tandem exchange C in the digit register and control circuit 304. The sender control circuit 300 then operates to transmit the impulses comprising the first digit by way of the line conductors C187 and C188 of the trunk line 793 to the toll selector switch 800, thereby to cause the line relay R820 in the toll selector switch 800 to operate intermittently, as previously explained, whereupon the vertical magnet M801 operates to drive the wiper set of the mechanism 801 in the vertical direction to the level in the main contact bank of the mechanism 801 wherein the trunk line extending to the C. A. X. trunk circuit individually associated with the first C. A. X. trunk extending between the central office A and the tandem exchange C is terminated. The sender control circuit 300 then operates to transmit the impulses comprising the second digit by way of the line conductors C187 and C188 of the trunk line 793 to the toll selector switch 800, thereby to cause the line relay R820 in the toll selector switch 800 to operate intermittently, as previously explained, whereupon the rotary magnet M802 operates to drive the wiper set of the mechanism 801 in the rotary direction to the position of the contact set in the main contact bank of the mechanism 801 terminating the trunk line extending to the C. A. X. trunk circuit individually associated with the first C. A. X. trunk in the group of C. A. X. trunks extending between the central office A and the tandem exchange C. At this time the subsequent operation of the toll selector switch 800 depends upon the idle or busy condition of the last-mentioned trunk line.

At the conclusion of the second digit transmitted to the toll selector switch 800, the line relay R820 reoperates. Also, at this time, the hold relay R830 and the relay R880 occupy their operated positions. Moreover, at this time, in the event the seized trunk line is idle, battery potential appears upon the control conductor thereof terminated by the contact engaged by the wiper 805 of the wiper set of the mechanism 801, thereby to complete the previously traced path for short-circuiting the winding of the relay R870 in order to prevent operation of the last-mentioned relay at this time. Shortly following the conclusion of the second digit transmitted to the toll selector switch 800, the relay R880 restores to complete, at RA881 and RC882, the previously traced circuit for energizing the upper winding of the electropolarized relay R810, thereby to cause the latter relay to operate.

Upon operating, the electropolarized relay R810 completes, at RA816, the previously traced holding circuit for energizing the intermediate winding thereof and causes the toll selector switch 800 to switch through and establish a connection 75 between the trunk line 793 extending to the toll

selector switch 800 and the seized trunk line, as previously explained.

However, in the event the trunk line seized by the toll selector switch 800 is busy at this time, ground potential appearing upon the control conductor thereof terminated by the contact engaged by the wiper 805 of the wiper set of the mechanism 801 completes the previously traced circuit for energizing the winding of the relay R870, thereby to cause the latter relay to operate. Upon operating, the relay R870 prepares, at RA872, a point in the previously traced holding circuit for energizing the winding thereof, prepares, at RA873, a point in the previously traced circuit for energizing the lower winding of the relay R860, interrupts, at RA871, a point in the previously traced circuit for illuminating the supervisory lamp L776, and completes, at RA874 and RA875, a circuit for energizing the winding of the relay R850, the last-mentioned circuit extending from ground potential appearing upon the contact engaged by the wiper 806 of the wiper set of the mechanism 801 and included in the contact set in the main contact bank of the mechanism 801 terminating the trunk line extending to the C. A. X. trunk circuit individually associated with the first C. A. X. trunk extending between the central office A and the tandem exchange C by way of the wiper 806, RA874, RA875, RA853, RC854, the resistor 826 and the winding of R850 to battery. When energized over the above-traced circuit, the relay R850 operates. Also, upon operating, the relay R870 interrupts, at RA877, a point in the previously traced circuit for energizing the upper winding of the relay R890 in series with the intermediate winding of the electropolarized relay R810, and prepares, at RA878, an alternative circuit for energizing the winding of the rotary magnet M802.

Upon operating, the relay R850 completes, at RA855 and at RA856 and RA857, the previously traced holding circuit for energizing the winding thereof, prepares, at RA853 and RC857', a holding circuit for energizing the upper winding of the relay R860, prepares at RA851, a holding circuit for energizing the winding of the relay R870, and interrupts, at RA854' and RC856', a point in the previously traced circuit for energizing the rotary magnet M802 in series with the relay R880. Also, the relay R850 prepares, at RA858 and RC858, at RA851' and RC852', and at RA854' and RC855', an alternative circuit for energizing the rotary magnet M802, and completes, at RA850, the previously traced path for connecting battery potential at the resistor 827 to the control conductor C189 of the trunk line 793. This application of battery potential to the control conductor C189 of the trunk line 793 prevents further operation of the sender control circuit 300 at this time, as previously noted.

Shortly following the conclusion of the second digit transmitted to the toll selector switch 800, the relay R880 restores to complete, at RA883 and RC884, the previously traced holding circuit for energizing the winding of the relay R870 and to complete, at RA855, the previously traced circuit for energizing the lower winding of the relay R860, thereby to cause the latter relay to operate. Upon operating, the relay R860 completes, at RA861 and RC863, a holding circuit for energizing the lower winding thereof, the last-mentioned circuit extending from ground at RA833 by way of C890, MA804, RA861 and RC863, RA885 and the lower winding of R860 to battery. Also, the relay R860 completes, at RA865 and RC866, 75

the previously traced alternative circuit for energizing the rotary magnet M802, thereby to cause the rotary magnet M802 to operate. Upon operating, the rotary magnet M802 interrupts, at 5 MA804, a point in the previously traced holding circuit for energizing the lower winding of the relay R860, thereby to cause the latter relay to restore. Upon restoring, the relay R860 interrupts, at RA865 and RC866, a point in the previously traced circuit for energizing the rotary magnet M802, thereby to cause the rotary magnet M802 to restore. Upon restoring, the rotary magnet M802 completes, at MA804, a point in the 10 previously traced original circuit for energizing the lower winding of the relay R860, thereby to cause the latter relay to operate. Each time the rotary magnet M802 is operated, the wiper set of the mechanism 801 is driven one step in the rotary direction, thereby to engage the next contact 15 set in the main contact bank of the mechanism 801 terminating the next trunk line extending to one of the dual call trunk circuits.

The rotary magnet M802 and the relay R860 continue to interact, in the above-described manner, until the wiper set of the mechanism 801 is driven into engagement with a contact set in the main contact bank of the mechanism 801 terminating an idle trunk line or until the wiper set is driven eleven steps away from its normal position. In the event the wiper set of the mechanism 801 is driven into engagement with a contact set in the main contact bank thereof terminating an idle trunk line, battery potential appearing upon the control conductor of the idle 30 trunk line engaged by the wiper 805 of the wiper set completes the previously traced circuit for energizing the upper winding of the electropolarized relay R810, thereby to cause the latter relay to operate. Upon operating, the electropolarized relay R810 interrupts, at RA817, a point in the previously traced alternative circuit for energizing the rotary magnet M802, as previously explained. Furthermore, the electropolarized relay R810 causes the toll selector switch 800 to switch 40 through and operatively to connect the trunk line 793 to the seized trunk line, whereupon the line relay R820, the hold relay R830, and the relays R850, R860 and R870 restore, as previously explained.

50 In the event that all of the trunk lines terminated in the level of the main contact bank of the mechanism 801 selected by the wiper set thereof are busy, the rotary magnet M802 and the relay R860 continue to interact, in the above-described manner, until the wiper set of the mechanism 801 is driven eleven steps from its normal position, as previously noted. When the wiper set of the mechanism 801 is driven eleven steps away from the normal position thereof, the set of switch springs S895 is actuated, thereby to interrupt, at the contact 897 thereof, a point in the previously traced original circuit for energizing the lower winding of the relay R860. Accordingly, the rotary magnet M802 does 55 not recomplete, at MA804, the previously traced original circuit for energizing the lower winding of the relay R860 when it restores, and the relay R860 is not reoperated at this time. However, upon restoring, the rotary magnet M802 completes, at MA803, the previously traced holding circuit for energizing the relay R870, thereby to retain the latter relay in its operated position at this time, and completes, at MA804, a circuit for energizing the upper winding of the relay 70 R840, the set of switch springs S895 being op-

erated to close the contact 896 thereof at this time. The last-mentioned circuit extends from ground at RA833 by way of C890, MA804, the contact 896 of the set of switch springs S895, and the upper winding of R840 to battery. When 5 energized over the above-traced circuit, the relay R840 operates.

Also, when the wiper set of the mechanism 801 is driven eleven steps from the normal position thereof, the set of switch springs S899 are actuated, thereby to prepare an alternative circuit for energizing the release magnet M805 of the mechanism 801, the last-mentioned circuit being completed, at RA846 and RC847, upon operation of the relay R840. The last-mentioned circuit 10 extends from ground at RA833 by way of C890, RA846, RC847, the set of switch springs S899, the set of switch springs S898, and the winding of M805 to battery. When energized over the above-traced circuit, the release magnet M805 15 operates. Also, upon operating, the relay R840 completes, at RA843 and RC845 and at RA846 and RC848, further points in the previously traced alternative circuit for energizing the rotary magnet M802 and completes, at RA843 and 20 RC844, an alternative circuit for energizing the vertical magnet M801. The last-mentioned circuit extends from ground at RA833 by way of C890, the resistor 825, RC858, RA858, RA843, RC844 and the winding of M801 to battery. The 25 energization of the vertical magnet M801 over the above-traced circuit including the resistor 825 prevents operation of the vertical magnet M801 and also prevents the wiper set of the mechanism 801 from being restored to its normal 30 vertical position incident to the operation of the release magnet M805. Also, upon operating, the relay R840 completes, at RA841, a holding circuit for energizing the upper winding thereof, the last-mentioned circuit extending from ground 35 at RA833 by way of C890, RA852, RC852, RA841, C891, MA801, C892 and the upper winding of R840 to battery.

Upon operating, the release magnet M805 releases the wiper set of the mechanism 801, thereby to cause the wiper set to be returned to its normal radial position. However, the wiper set of the mechanism 801 is not returned to its normal vertical position due to the completed circuit for energizing the winding thereof by 40 way of the resistor 825. When the wiper set of the mechanism 801 is returned to its normal rotary position, the vertical control wiper 807 thereof engages an associated contact in the upper section 821 of the vertical control contact bank, thereby to complete a circuit for fully energizing the winding of the vertical magnet M801, the last-mentioned circuit extending from ground 45 at RA833 by way of C890, RA852, RC852, RA841, C891, the contact 812 of the set of switch springs 50 S810, the vertical control wiper 807, the associated contact in the upper section 821 of the vertical control contact bank, and the winding of M801 to battery. When energized over the above-traced circuit, the vertical magnet M801 55 fully operates to drive the wiper set of the mechanism 801 an additional step in the vertical direction. When the wiper set of the mechanism 801 is returned to its normal radial position, the set of switch springs S899 is actuated, thereby to 60 interrupt the previously traced circuit for energizing the release magnet M805 of the mechanism 801. Also, when the wiper set of the mechanism 801 is returned to its normal radial position, the set of switch springs S895 is actuated, 65

thereby to interrupt, at the contact 896 thereof, the above-traced original circuit for energizing the upper winding of the relay R840, the last-mentioned relay being held in its operated position 5 at this time due to the completed holding circuit for energizing the lower winding thereof. Also, when the set of switch springs S895 is actuated, as noted above, the previously traced original circuit for energizing the lower winding of the relay R860 is completed, at the contact 897 thereof, thereby to cause the relay R860 to operate and complete, at RA861 and RC863, the previously traced holding circuit for energizing the lower winding thereof.

15 Also, upon operating, the vertical magnet M801 interrupts, at MA801, a point in the previously traced holding circuit for energizing the upper winding of the relay R840. Shortly thereafter the relay R840, being of the slow-to-release type, 20 restores to interrupt, at RA841, an additional point in the previously traced holding circuit for energizing the upper winding thereof and interrupts, at RA841, a point in the previously traced circuit for energizing the vertical magnet M801 25 by way of the vertical control contact 807. Also, upon restoring, the relay R840 interrupts, at RA843 and RC844, the previously traced circuit for energizing the vertical magnet M801 by way of the resistor 825, thereby to cause the vertical 30 magnet M801 to release. Moreover, the relay R840 completes, at RA843 and RC845 and at RA846 and RC848, the previously traced alternative circuit for energizing the rotary magnet M802, thereby to cause the rotary magnet M802 35 to operate and drive the wiper set of the mechanism 801 away from its normal position one step in the rotary direction. At this time the wiper set of the mechanism 801 engages the contact set in the main contact bank of the mechanism 801 40 terminating the first trunk line in the succeeding level of the main contact bank and extending to one of the C. A. X. trunk circuits. The subsequent operation of the toll selector switch 800 depends upon the idle or busy condition of the 45 seized trunk line, as previously explained. In the event the seized trunk line is idle, the electropolarized relay R810 operates, as previously described, thereby to cause the toll selector switch 800 to switch through and connect the 50 trunk line 793 to the seized trunk line.

However, in the event the seized trunk line is busy, the rotary magnet M802 and the relay R860 interact, in the previously described manner, thereby to cause the wiper set of the mechanism 801 to be driven step by step in the rotary direction in order to test successively the idle or busy conditions of the successive trunk lines.

The trunk lines extending to the C. A. X. trunk circuits individually associated with the group 60 of C. A. X. trunks extending between the central office A and the tandem exchange C may be terminated in contact sets disposed in several different levels in the main contact bank of the mechanism 801. In this event, the toll selector switch 800 continues to operate, first to test successively the trunk lines in any given level, then to return the wiper set of the mechanism 801 thereof to its normal rotary position and subsequently drive the wiper set of the mechanism 801 to the next adjacent level in the main contact bank of the mechanism 801, and finally to test successively the adjacent trunk lines in the selected level.

The toll selector switch 800 continues to operate, as previously explained, until an idle trunk

line is seized thereby or until the last trunk line in the last level is seized thereby and found to be busy. The operation of the toll selector switch 800 to cause the supervisory lamp L176 to flash when the last busy trunk line in the last level is 5 tested is the same as that previously explained, thereby to indicate to the operator at the first operator position that all of the C. A. X. trunks extending between the central office A and the tandem exchange C are busy at this time. 10

Continuing now with the supervision and release of the established connection between the finder-selector link illustrated and the subscriber substation T3 in the tandem exchange C, it is noted that the supervision of this established 15 connection is the same as that previously explained. Furthermore, the release of this established connection is effected in the previously described manner.

It is noted that when the operator at the first 20 operator position 1400 causes the toll selector switch 800 to be released, ground potential is removed from the control conductor C684 of the trunk line 680, thereby to interrupt the previously traced circuit for energizing the lower winding 25 of the relay R610 in the dual call trunk circuit 600. When the last-mentioned circuit is interrupted, the relay R610 restores to interrupt, at RA614 and RA615, a further point in the holding circuit for energizing the lower winding 30 thereof, to interrupt, at RA610 and RC619, a point in the previously traced path for applying battery potential at the resistor 685 to the control conductor C636, and to complete, at RA610 and RC618, the previously traced path for applying 35 ground potential at RC659 to the control conductor C636. At this time the C. A. X. trunk circuit 600 is completely released. Also, when ground potential is applied to the control conductor C636, the dual call control circuit and repeater 500 in the tandem exchange C is controlled by way of the simplex link including the C. A. X. trunk 510, thereby to cause the dual call control circuit and repeater 500 to be released and marked as idle to the switching apparatus in the C. A. X. network having access thereto, thereby to render the C. A. X. trunk 510 available for further use. The release of the selector switch 516 and the connector switch 519 in the tandem exchange C is effected in the usual 50 manner in response to the release of the dual call control circuit and repeater 500.

Extension of a reverting call from the switchboard to the C. A. X. network

As previously noted, the local subscribers in the exchanges D and E and in the tandem exchange C have direct access to the local switch trains in the respective exchanges which have access only to other local subscriber lines and to 60 trunk circuits in the tandem exchange C. Accordingly, a subscriber at a calling subscriber substation in one of the exchanges mentioned cannot complete a connection to a subscriber substation in a different one of the exchanges 65 mentioned unassisted, as this type of connection must be completed with the assistance of an operator at one of the operator positions in the central office A. For example, in order to extend a connection from the subscriber substation T3 in 70 the tandem exchange C to a subscriber substation in the exchange D, the subscriber at the substation T3 first initiates a call to the switchboard in the central office A, as previously explained. Assuming that the call is routed by way 75

of the dual call control circuit and repeater 500, the C. A. X. trunk 510 extending between the tandem exchange C and the central office A, the C. A. X. trunk circuit 600, the trunk 670, and 5 the finder switch 700 of the finder-selector link illustrated to the first operator position 1400, the operator at the first operator position answers the call, in the previously described manner, and is advised by the subscriber at the substation T3 10 that the call is to be extended to a subscriber substation in the exchange D.

Ordinary calls routed from the C. A. X. network to the first operator position by way of the finder switch 700 are extended, after they have 15 been answered at the first operator position, by way of the toll selector switch 800 to their destination in the previously described manner. However, when the call is to be extended back into the C. A. X. network, the operator at the 20 first operator position does not set up the call by way of the toll selector switch 800 but sets up the call as a reverting call back over the C. A. X. trunk 510 by way of the finder switch 700 in a manner more fully described subsequently. This 25 arrangement provides for the completion of the call directly in the tandem exchange C, the C. A. X. trunk 510 extending between the tandem exchange C and the central office A being utilized only for supervisory and release purposes. Accordingly, a substantial saving in the number of 30 trunks extending between the tandem exchange C and the central office A is effected.

When the finder switch 700 of the finder-selector link illustrated operates to seize the trunk line 670 extending to the C. A. X. trunk circuit 600, the marking relay R650 operates to complete, at RA651, the previously traced holding circuit for energizing the upper winding thereof, to complete, at RA654 and RC654, the previously traced path for applying ground potential to the control conductor C684 of the trunk line 680 in order to mark the last-mentioned trunk line as busy to the switches having access thereto, to interrupt, at RA656 and RC657, the previously traced circuit for energizing the start relay R640 in order to cause the latter relay to restore, to prepare, at RA656 and RC656, the previously traced path for applying ground potential to the control conductor C675 of the trunk line 670 in order to prepare the previously traced circuit for illuminating the supervisory lamp L767, to interrupt, at RA658 and RC659, the previously traced circuit for energizing the relay R630 in order to cause the latter relay to restore, and to complete, at RA658 and RC658, the previously traced path for applying battery potential at the resistor 685 to the control conductor C636. Upon restoring, the relay R630 interrupts, at RA632, the previously traced path for applying ground potential to the control conductor C675 of the trunk line 670, thereby to interrupt a path for short-circuiting the winding of the relay R660, the last-mentioned path extending, when completed, from ground at RA617 by way of RA620, RA632, RA656, RC656, 65 C875 and the winding of R660 to ground. When the previously traced path for applying ground potential to the control conductor C675 of the trunk line 670 is interrupted, the winding of the relay R660 is energized in series with the supervisory relay R1230 in the relay group 1200A. When the relay R660 in the trunk circuit 600 is thus energized, it operates; however, the relay R1230 in the relay group 1200A does not operate due to the high series resistance of the winding 70 of the relay R660. Accordingly, the supervisory

lamp L767 is not illuminated at this time. Upon operating, the relay R660 in the trunk circuit 600 interrupts, at RA661, a point in a circuit, traced hereinafter, for energizing in multiple the upper and lower windings of the dial-out relay R620. 5 At this time the talk relay R1130 and the answer pilot relay R1260 in the relay group 1200A occupy their operated positions.

After the operator at the first operator position is advised that the call is to be extended to 10 the distant exchange D in the C. A. X. network, she initiates the reverting call by operating the dial rear key K4 away from its normal position. When the dial rear key K4 is operated away from its normal position, an obvious circuit is completed, at the contact 1444 thereof, for energizing the relay R1350, thereby to cause the latter relay to operate. Upon operating, the relay R1350 interrupts, at RA1352, a point in the previously traced path for applying ground potential 15 at RA1101 to the start conductor C1360 included in the cable 1367 extending to the sender control circuit 300, thereby to cause the sender control circuit 300 to be released. Also, the relay R1350 prepares, at RA1353, an alternative circuit for 20 applying ground potential to the start conductor C1360 and completes, at RA1351, a circuit for energizing the lower winding of the call relay R1340 in series with the lower winding of the call pilot relay R1320, thereby to cause the last- 25 mentioned relays to operate. Upon operating, the call pilot relay R1320 interrupts, at RA1321, a further point in the previously traced circuit for 30 energizing the distributor start relay R1310 and 35 interrupts, at RA1322, a further point in the previously traced circuit for applying ground potential to the start conductor C1360. Upon operating, the call relay R1340 completes, at RA1345, a holding circuit for energizing the upper winding thereof, the last-mentioned circuit extending 40 from ground at RA1264 by way of C1379, RA1332, RA1345 and the upper winding of R1340 to battery. Also, the relay R1340 completes, at RA1349, an alternative path for applying ground potential 45 to the start conductor C1360 included in the cable 1367 extending to the sender control circuit 300, this path extending from ground at RA1101 by way of RA137, RC1138, C1187, RA1273, RA1267, C1386, RA1349, RA1353 and RA1336 to the start conductor C1360. This application of 50 ground potential to the start conductor C1360 causes the sender control circuit 300 to operate, thereby to cause the rotary switch 301 thereof to operate and search for one of the cables having 55 a calling condition thereon. Also, upon operating, the relay R1340 interrupts, at RA1341 and RC1342, the normally completed path for applying ground potential to the guard conductor C1362 included in the cable 1367, thereby to mark the cable 1367 as having a calling condition there- 60 on. Also, the relay R1340 interrupts, at RA1346 and RC1348, a point in the previously traced path for applying battery potential at the supervisory relay R1230 to the wiper 706 of the wiper set of the mechanism 701 in the finder switch 700. 65 When battery potential is thus removed from the wiper 706 of the wiper set of the mechanism 701, the previously traced circuit for energizing the relay R660 in the C. A. X. trunk circuit is interrupted, thereby to cause the latter relay to 70 restore. Further, the relay R1340 prepares, at RA1346 and RC1347, a point in an alternative circuit, traced hereinafter, for energizing the relay R660 in the C. A. X. trunk circuit 600, completes, at RA1341 and RC1343, an obvious circuit 75

for energizing the rear split relay R1220 in order to cause the latter relay to operate, and completes, at RA1344, an alternative circuit for energizing the upper winding of the connect relay R750 in the finder switch 700 in series with the winding of the talk relay R1130. The last-mentioned circuit extends from ground at the winding of the talk relay R1130, by way of the winding of R1130, C1183, RA1344, the conductor 10 C1378 in the cable 1286, RA1759, RA1750 and the upper winding of R750 to battery.

As previously noted, the sender control circuit 300 operates to find the cable 1367 having a calling condition thereon, at which time an impulsive loop is completed in the sender control circuit 300 by way of the trunk circuit at the first operator position to the wipers 702 and 703 of the wiper set of the mechanism 701 in the finder switch 700 subsequent to the operation of the front split relay R1210 in the relay group 1200A. The wiper 702 of the wiper set of the mechanism 701 is connected by way of RA741, RA753, RA752, the conductor C1275 in the cable 1286, RA1224, RC1226, RA1241, and RC1242 to the line conductor C1365 of the trunk circuit at the first operator position; and the wiper 703 of the wiper set of the mechanism 701 is connected by way of RA742, RA756, RA755, the conductor C1276 in the cable 1286, RA1221 and RC1223 to the line conductor C1366 of the trunk circuit at the first operator position, the line conductors C1365 and C1366 of the trunk circuit at the first operator position being included in the cable 1367 extending to the sender control circuit 300 and an impulsive loop being completed therebetween in the sender control circuit 300. Also, when the sender control circuit 300 seizes the cable 1367 having the calling condition thereon, it operates to cause ground potential to be applied to the control conductor C1363 in the cable 1367. This application of ground potential to the control conductor C1363 completes a circuit for energizing the relay R1300 in the relay group 1200A in series with the dial-out relay R620 in the C. A. X. trunk circuit 600, this circuit extending from the grounded control conductor C1363 by way of RA1331, C1377, the winding of R1300, the conductor C1380 in the cable 1286, RA141, RA143, the wiper 704 of the wiper set of the mechanism 701 in the finder switch 700, and the control conductor C674 of the trunk line 670 to RA661; from RA661 by way of the lower winding of R620 to battery; and from RA661 by way of RA629 and the upper winding of R620 to battery. It is noted that the last-mentioned circuit is prepared, at RA661, incident to the restoration of the relay R660 in the C. A. X. trunk circuit 600. When energized over the above-traced circuit, the relay R1300 in the relay group 1200A and the dial-out relay R620 in the C. A. X. trunk circuit 600 operate. Upon operating, the relay R1300 interrupts, at RA1301, a point in the previously traced circuit for energizing the error relay R1270 in the relay group 1200A, thereby to prevent operation of the last-mentioned relay at this time.

Upon operating, the dial-out relay R620 interrupts at RA622 and RC623 and at RA627 and RC628, the previously traced connection between the line conductors C671 and C672 of the trunk line 670 and the repeater 633 and completes, at RA621 and RA622, at RA623 and RA624, and at RA626 and RA627, an alternative path for applying battery at the resistor 632 to the control conductor C636. The last-mentioned path extends

from battery at the resistor 632, by way of the resistor 632, RA626 and RA627 to the line conductor C672 of the trunk line 670 and from the control conductor C636 by way of RA624, RA623, RA621 and RA622 to the line conductor C671 of the trunk line 670, the line conductors C672 and C671 of the trunk line 670 being engaged by the wipers 703 and 702, respectively, of the wiper set of the mechanism 701 in the finder switch 700 at this time. Accordingly, at this time an impulsive loop is completed from battery at the resistor 632 by way of the previously traced circuit including the finder switch 700, the trunk circuit at the first operator position and the sender control circuit 300 to the control conductor C636.

Furthermore, it is noted that, upon operating, the dial-out relay R620 in the dual call trunk circuit 600 interrupts, at RA624 and RC625, the previously traced path for applying battery potential at the resistor 685 to the control conductor C636, the last-mentioned path being completed, at RA658 and RC658, incident to the operation of the marking relay R650. When the previously traced path for applying battery potential to the control conductor C636 is completed, at RA658 and RC658, battery potential is conducted by way of the simplex link including the C. A. X. trunk 510 to the control conductor C515 extending to the dual call control circuit 30 and repeater 500 in the tandem exchange C. This application of battery potential causes the dual call control circuit and repeater 500 to operate and render the selector switch 517 operative in response to impulses transmitted thereby by way of the trunk line 502 extending between the selector switch 517 and the dual call control circuit and repeater 500.

Subsequent to the operation of the dial-out relay R620 in the C. A. X. trunk circuit 600, battery potential at the resistor 632 is connected by way of the previously traced path to the control conductor C636 and therefrom by way of the simplex link including the C. A. X. trunk 510 to the control conductor C515 extending to the dual call control circuit and repeater 500. At this time the dual call control circuit and repeater 500 is effective to cause impulses transmitted thereto by way of the control conductor C515 to be transmitted by way of the trunk line 502 to the selector switch 517.

The operator at the first operator position then actuates the sending key set 303 in order to register in the digit register and control circuit 304 operatively associated with the sending key set 303 and the sender control circuit 300 a predetermined series of digits corresponding to the directory number of the called subscriber substation in the exchange D, whereupon the sender control circuit 300 begins to operate, thereby to transmit the impulses comprising the first digit by way of the previously traced connections comprising the simplex link including the C. A. X. trunk 510 to the dual call control circuit and repeater 500. More specifically, the sender control circuit 300 operates intermittently to interrupt the previously traced connections for applying battery potential to the control conductor C515 extending to the dual call control circuit and repeater 500, thereby to cause impulses to be transmitted to the dual call control circuit and repeater 500, and therefrom by way of the trunk line 502 to the selector switch 517. The impulses transmitted to the selector switch 517 cause this switch to operate and select the group 75

of trunk lines extending from the tandem exchange C to the exchange D. Subsequently, the selector switch 517 operates automatically, thereby to seize an idle trunk line in this group, such, for example, as the trunk line 532. Assuming that the selector switch 517 operates to seize the trunk line 532, the local switch train included in the exchange D then operates to become responsive to subsequent impulses transmitted thereto.

The sender control circuit 300 then operates, thereby to cause the impulses comprising the subsequent digits to be transmitted by way of the previously traced connections to the dual call control circuit and repeater 500 in the tandem exchange C from which the impulses comprising the digits are transmitted by way of the trunk line 502, the selector switch 517, and the trunk line 532 to the local switch train in the exchange D, thereby to cause the local switch train in the exchange D to operate and seize the called subscriber line. The subsequent operation of the local switch train in the exchange D depends upon the idle or busy condition of the called subscriber line in accordance with conventional practice.

As previously noted, immediately the operator at the first operator position 1400 begins to operate the sending key set 303 in order to cause the digits to be registered in the digit register and control circuit 304, the digit register and control circuit 304 begins to operate, thereby to cause the sender control circuit 300 to transmit the digits over the C. A. X. trunk 510. Accordingly, in the event the operator at the first operator position makes an error in operating the sending key set 303, it is necessary for the partially operated apparatus in the tandem exchange C to be released, this apparatus being partially operated at this time due to the fact that one or more digits have been transmitted thereto by way of the C. A. X. trunk 510. Furthermore, it is necessary that the digit register and control circuit 304 be cleared of any digits registered therein.

This is accomplished by returning the dial rear key K4 to its normal position and operating the dual release key K11 away from its normal position. When the dual release key K11 is operated away from its normal position, an obvious alternative circuit is completed, at the contact 1429 thereof, for energizing the rear split relay R1220, thereby to retain the last-mentioned relay in its operated position. Also, at the contact 1427 of the dual release key K11, an obvious circuit is completed for energizing the relay R1240, thereby to cause the latter relay to operate. Moreover, at the contact 1428 of the dual release key K11, an obvious path is completed for applying ground potential to the line conductor C1365 of the trunk circuit at the first operator position. Upon operating, the relay R1240 interrupts, at RA1241 and RC1242, a point in the previously traced path for applying battery potential to the control conductor C636 and completes, at RA1241 and RC1243, a path for applying ground potential to the control conductor C636. The last-mentioned path extends from ground at RC1243 by way of RA1241, RC1226, RA1224, the conductor C1275 in the cable 1286, RA752, RA753, RA711, the wiper 702 of the wiper set of the mechanism 701, the line conductor C671 of the trunk line 670, RA622, RA621, RA623 and RA624 to the control conductor C636. This application of ground potential to the control conductor C636 is forwarded by way of the previously

traced path comprising the simplex link including the C. A. X. trunk 510 to the control conductor C515 extending to the dual call control circuit and repeater 500, thereby to cause the dual call control circuit and repeater 500 to operate and effect the release of the selector switch 517 and the local switch train in the exchange D associated therewith. Also, the relay R1240 completes, at RA1244, an alternative circuit for energizing the relay R1300 in the relay group 1200A in series with the dial-out relay R620 in the C. A. X. trunk circuit 600, the last-mentioned circuit extending from ground at RA1244 by way of C1371, the winding of R1300, the conductor C1380 in the cable 1286, RA741, RA713, the wiper 704 of the wiper set of the mechanism 701, the control conductor C674 of the trunk line 670, RA661 and the lower winding of R620 to battery. The completed circuit, traced above, prevents the restoration of the relay R1300 in the relay group 1200A and the dial-out relay R620 in the C. A. X. trunk circuit 600 at this time. The application of ground potential to the line conductor C1365 of the trunk circuit at the first operator position completes a path extending by way of the above-traced connections including the sender control circuit 300 and the finder switch 700 for applying ground potential to the line conductor C672 of the trunk line 670. This application of ground potential to the line conductor C672 of the trunk line 670 further insures that the battery potential at the resistor 632 is not conducted therefrom forwardly into the trunk circuit at the first operator position.

When the dial rear key K4 is returned to its normal position, the previously mentioned circuit for energizing the relay R1350 is interrupted, at the contact 1444 thereof, thereby to cause the latter relay to restore. Upon restoring, the relay R1350 interrupts, at RA1353, the previously traced path for applying ground potential to the start conductor C1360 included in the cable 1367 extending to the sender control circuit 300. When ground potential is removed from the start conductor C1360, the sender control circuit 300 is caused to release. Also, upon restoring, the relay R1350 interrupts, at RA1351, the previously traced circuit for energizing in series with the lower winding of the call relay R1340 and the lower winding of the call pilot relay R1320. Shortly after the last-mentioned circuit is interrupted, the call pilot relay R1320, being of the slow-to-release type, restores. However, the call relay R1340 does not restore due to the previously traced completed holding circuit for energizing the upper winding thereof.

After operating the dial rear key K4 to its normal position, the operator at the first operator position 1400 reoperates the dial rear key K4 away from its normal position, thereby the recomplete the previously traced circuit for energizing the relay R1350. The relay R1350 then reoperates, thereby to complete, at RA1351, the previously traced circuit for energizing the lower winding of the call relay R1340 in series with the lower winding of the call pilot relay R1320, the call relay R1340 being operated at this time. Also, the relay R1350 completes, at RA1353, the previously traced path for applying ground potential at RA1101 to the start conductor C1360 included in the cable 1367 extending to the sender control circuit 300. This application of ground potential to the start conductor C1360 causes the sender control circuit 300 to operate in order to hunt for a cable having a calling condition thereon. Subsequently the 75

sender control circuit 300 operates to seize the cable 1367 as previously explained.

The operator at the first operator position 1400 then operates the dual release key K11 back to its normal position, thereby to interrupt, at the contact 1427 thereof, the previously mentioned circuit for energizing the relay R1240 in order to cause the last-mentioned relay to restore shortly thereafter, this relay being of the slow-to-release type. Also, when the dual release key K11 is returned to its normal position, the previously traced path for applying ground potential to the line conductor C1365 of the trunk circuit at the first operator position is interrupted, at the contact 1428 thereof and the previously traced alternative circuit for energizing the rear split relay R1220 is interrupted at the contact 1429 thereof. However, the rear split relay R1220 remains in its operated position at this time due to the circuit for energizing the winding thereof completed at RA1341 and RC1343 of the call relay R1340.

Upon restoring, the relay R1240 interrupts, at RA1241 and RC1243, a point in the previously traced path for applying ground potential to the control conductor C636 and recompletes, at RA1241 and RC1242, the previously traced path for applying battery potential at the resistor 632 to the control conductor C636 by way of the finder switch 700 and the sender control circuit 300. Further, the relay R1240 interrupts, at RA1244, a point in the alternative circuit for energizing the relay R1300 in the relay group 1200A in series with the dial-out relay R620 in the dual call trunk circuit 600, the last-mentioned relays being retained in their operated positions at this time due to the circuit for energizing the windings thereof completed in the sender control circuit 300. At this time the apparatus is in condition to initiate the extension of the call from the first operator position 1400 to the tandem exchange C as explained above. The operator at the first operator position 1400 then reoperates the sending key set 303, thereby to cause the proper directory number of the called subscriber substation in the exchange D to be registered in the digit register and control circuit 304. The digit register and control circuit 304 then operates to cause the sender control circuit 300 to operate and transmit the digits over the previously traced connections to the tandem exchange C. The apparatus in the tandem exchange C then operates, thereby to cause the local switch train in the exchange D to operate and seize the called subscriber line as previously explained.

After the sender control circuit 300 operates to transmit the entire series of digits, it operates to cause ground potential to be applied to the conductor C1364 included in the cable 1367. This application of ground potential to the conductor C1364 completes an obvious circuit for energizing the cut-in relay R1330, in order to cause this relay to operate.

Upon operating, the cut-in relay R1330 completes, at RA1333 and RA1334, a holding circuit for energizing the winding thereof, this circuit extending from ground at RA1351 by way of RA1334, RA1333 and the winding of R1330 to battery. Also, the cut-in relay R1330 interrupts, at RA1334 and RC1335, a point in the previously traced circuit for energizing the lower winding of the call relay R1340 in series with the lower winding of the call pilot relay R1320 and interrupts, at RA1332, a point in the previously traced holding circuit for energizing the upper winding

of the call relay R1340, thereby to cause the call relay R1340 and the call pilot relay R1320 to restore. Furthermore, the cut-in relay R1330 interrupts, at RA1331, a point in the previously traced circuit for energizing the relay R1300 in the relay group 1200A in series with the lower winding of the dial-out relay R620 in the C. A. X. trunk circuit 600, thereby to cause the latter relays to restore, and interrupts, at RA1336, a point in the previously traced circuit for applying ground potential to the start conductor C1360 included in the cable 1367 extending to the sender control circuit 300. Upon restoring, the call pilot relay R1320 prepares, at RA1321, a point in the previously traced circuit for energizing the distributor start relay R1310. Upon restoring, the call relay R1340 interrupts, at RA1345, a further point in the holding circuit for energizing the upper winding thereof, completes, at RA1341 and RC1342, the previously mentioned path for applying ground potential to the guard conductor C1362 included in the cable 1367 extending to the sender control circuit 300, thereby to remove the previous marking of the cable 1367 as having a calling condition thereon, and interrupts, at RA1341 and RC1343, a point in the previously traced circuit for energizing the rear split relay R1220, thereby to cause the latter relay to restore shortly thereafter. Also, upon restoring, the call relay R1340 interrupts, at RA1344, the alternative circuit for energizing the talk relay R1130 in the relay group 1200A in series with the upper winding of the connect relay R750 of the finder switch 700, interrupts, at RA1346 and RC1347, the connection between the conductor C1383 in the cable 1286 and the conductor C1361 in the cable 1367, and completes, at RA1346 and RC1348, the previously traced holding circuit for energizing the relay R660 in the C. A. X. trunk circuit 600 in series with the supervisory relay R1230 in the relay group 1200A. As previously noted, the supervisory relay R1230 in the relay group 1200A does not operate in series with the relay R660 in the C. A. X. trunk circuit 600; however, the last-mentioned relay remains in its operated position at this time. Also, the call relay R1340 interrupts, at RA1349, a point in the previously traced path for applying ground potential to the start conductor C1360 included in the cable 1367.

Also, it is noted that immediately the sender control circuit 300 operates to transmit the entire series of digits by way of the previously traced connections over the C. A. X. trunk 510, it operates to cause battery potential to be applied to the conductor C1361 in the cable 1367, thereby to complete a circuit for energizing the relay R660 in the C. A. X. trunk circuit 600, this circuit extending from battery potential appearing upon the conductor C1361 included in the cable 1367 by way of RC1347, RA1346, the conductor C1383 in the cable 1286, RA743, RA744, RA747, the wiper 706 of the wiper set of the mechanism 701, the control conductor C675 of the trunk line 670, and the winding of R660 to ground. When energized over the above-traced circuit, the relay R660 in the C. A. X. trunk circuit 600 operates. As previously noted, upon restoring, the call relay R1340 interrupts, at RA1346 and RC1347, the above-traced circuit for energizing the relay R660 and completes, at RA1346 and RC1348, a holding circuit for energizing the relay R660. Accordingly, the relay R660 remains in its operated position. Upon operating, the relay R660 interrupts, at RA661, a further point in the previously traced

circuit for energizing the dial-out relay R620 in the dual call trunk circuit 600, thereby to cause the latter relay to restore.

Upon restoring, the dial-out relay R620 in the 5 C. A. X. trunk circuit 600 interrupts, at RA621 and RA622, at RA623 and RA624, and at RA626 and RA627, the previously traced path for applying battery potential at the resistor 632 to the control conductor C636, completes, at RA624 and 10 RC625, the previously traced path for applying battery potential at the resistor 685 to the control conductor C636, and completes, at RA622 and RC623 and at RA627 and RC628, the previously traced connection between the repeater 633 and 15 the line conductors C671 and C672 of the trunk line 670.

Upon restoring, the rear split relay R1220 in the relay group 1200A interrupts, at RA1221 and RC1223 and at RA1224 and RC1226, further 20 points in the previously traced path for applying battery potential at the resistor 632 to the control conductor C636 and completes, at RA1221 and RC1222 and at RA1224 and RC1225, an operative connection between the C. A. X. trunk 25 510 and the trunk circuit at the first operator position 1400. At this time the line conductors C1180 and C1181 of the trunk circuit at the first operator position are operatively connected to the conductors C1278 and C1277 included in the cable 30 1286, the last-mentioned conductors being connected to the wipers 703 and 702, respectively, of the wiper set of the mechanism 701 in the finder switch 700 by way of the previously traced path. Furthermore, the talking repeater 1106 at the 35 first operator position is operatively connected by way of the previously traced connections to the line conductors C1180 and C1181 of the trunk circuit thereat; and the wipers 702 and 703 of the wiper set of the mechanism 701 in the finder 40 switch 700 are operatively connected to the line conductors C671 and C672 of the trunk line 670, the last-mentioned line conductors of the trunk line 670 being operatively connected to the repeater 633 by way of the previously traced connections. Also, the repeater 633 is connected by 45 way of the C. A. X. trunk 510 and the trunk line 504 to the dual call control circuit and repeater 500, the dual call control circuit and repeater 500 being connected by way of the trunk line 502, the 50 selector switch 517, the trunk line 532, and the local switch train in the exchange D to the called subscriber line.

After the entire series of digits has been transmitted to the dual call control circuit and repeater 500, the dual call control circuit and repeater 500 operates to cause ground potential to be applied to the control conductor C515, thereby to complete the previously traced path comprising the simplex link including the C. A. X. trunk 510 55 for connecting ground potential to the control conductor C636. This application of ground potential to the control conductor C636 completes the previously traced circuit for energizing the relay R630 in the C. A. X. trunk circuit 600, thereby to cause the latter relay to operate. Upon operating, the relay R630 completes, at RA632, the previously traced path for applying ground potential at RA617 to the control conductor C675 of the trunk line 670. This application of ground 60 potential to the control conductor C675 completes the previously traced path for short-circuiting the winding of the relay R660 in the C. A. X. trunk circuit 600 and completes the previously traced circuit for energizing the supervisory relay R1230 65 in the relay group 1200A, thereby to cause the re-

lay R660 to restore and to cause the supervisory relay R1230 to operate. Upon operating, the supervisory relay R1230 completes, at RA1231, the previously traced circuit for illuminating the supervisory lamp L767. The illumination of the supervisory lamp L767 indicates to the operator at the first operator position that the call has been extended by way of the C. A. X. network to the called subscriber line.

As previously noted, in the event the called subscriber line is busy, the connector switch in the local switch train in the exchange D operates to cause busy tone current to be returned over the trunk line 532 from the exchange D to the tandem exchange C, this busy tone current being returned 15 from the trunk line 532 by way of the previously traced connections to the talking repeater 1106, thereby to cause the receiver of the telephone instrument at the first operator position to operate and give the operator thereat busy tone indication. Also, it is noted that the trunk lines 502 and 503 extending to the dual call control circuit and repeater 500 are operatively connected at this time. Accordingly, a portion of the busy tone current returned over the trunk line 532 extending 20 between the exchange D and the tandem exchange C is conducted by way of the selector switch 517, the trunk line 502, and the dual call control circuit and repeater 500 to the trunk line 503 and from the trunk line 503 to the calling 25 subscriber substation T3. This busy tone current returned to the calling subscriber substation T3 indicates to the subscriber thereat that the called subscriber line is busy at this time. At this time the operator at the first operator position 30 may release the outgoing end of the reverting call connection including the selector switch 517 in the tandem exchange C and the local switch train in the exchange D in a manner more fully described subsequently.

Assuming that the called subscriber line terminating in the exchange D is idle at this time, when the subscriber at the called subscriber substation answers the call, an established connection is completed from the calling subscriber 45 substation T3 in the tandem exchange C to the called subscriber substation in the exchange D, the last-mentioned connection extending from the subscriber substation T3 by way of the subscriber line 533, the line switch 520, the selector 50 switch 518, the trunk line 503, the dual call control circuit and repeater 500, the trunk line 502, the selector switch 517, the trunk line 532 extending to the exchange D, the local switch train in the exchange D, and the calling subscriber 55 line to the called subscriber substation. Also, when the call is answered at the called subscriber substation, the dual call control circuit and repeater 500 operates to cause battery potential to be applied to the control conductor C515, thereby to cause ground potential to be applied by way of the simplex link including the C. A. X. trunk 510 to the control conductor C636. This application of battery potential to the control conductor C636 completes the previously traced 60 path for short-circuiting the winding of the relay R630 in the dual call trunk circuit 600, thereby to cause the latter relay to restore. Upon restoring, the relay R630 interrupts, at RA632, the previously traced path for applying ground 65 potential to the control conductor C675 of the trunk line 670, thereby to cause the supervisory lamp L767 to be extinguished in order to indicate to the operator at the first operator position that the subscriber at the called subscriber substa- 70

75

tion in the exchange D has answered the dual call extending thereto.

After the operator at the first operator position has extended the dual call connection to the exchange D, she returns the dial rear key K4 to its normal position, thereby to interrupt, at the contact 1444 thereof, the previously mentioned circuit for energizing the relay R1350, whereupon the latter relay restores. Upon restoring, the relay R1350 interrupts, at RA1351, the previously traced holding circuit for energizing the cut-in relay R1330, thereby to cause the latter relay to restore. Upon restoring, the cut-in relay R1330 interrupts, at RA1333 and RA1334, a further point in the holding circuit for energizing the winding thereof.

The supervision of the dual call by way of the C. A. X. trunk 510 is the same as that previously explained. It is noted that both the calling and the called parties have switchhook supervision and may signal the operator at the first operator position 1400. When either the calling or the called party wishes to signal the operator at the first operator position, he intermittently operates the switchhook at his substation, thereby to cause the dual call control circuit and repeater 500 to operate and intermittently to apply ground potential to the control conductor C515. The application of ground potential to the control conductor C515 is extended by way of the simplex link including the C. A. X. trunk 510 to the control conductor C636, thereby to cause the relay R630 in the C. A. X. trunk circuit 600 to operate. Upon operating, the relay R630 completes, at RA632, the previously traced path for applying ground potential to the control conductor C675 of the trunk line 670, this application of ground potential to the control conductor C675 being effective to cause the supervisory lamp L767 to be illuminated regardless of the position of the talk key 780 of the finder switch 700, as previously explained. The flashing of the supervisory lamp L767 indicates to the operator at the first operator position that one of the parties communicating over the dual call connection including the C. A. X. trunk 510 wishes to communicate with her. The operator at the first operator position 1400 then operates the talk key 780 of the finder switch 700 away from its normal position, thereby operatively to associate the trunk circuit at her position and the talking repeater 1106 associated therewith with the C. A. X. trunk circuit 600, as previously explained.

The release of the dual call connection is primarily under the control of the operator at the first operator position 1400 and when either the calling or the called party replaces the receiver of the telephone instrument at his substation upon its switchhook, the dual call control circuit and repeater 500 operates to cause ground potential to be applied to the control conductor C515 as previously noted. This application of ground potential to the control conductor C515 completes the previously traced circuit for energizing the relay R630 in the C. A. X. trunk circuit 600 in order to cause the supervisory lamp L767 to be illuminated. The operator at the first operator position then operates the talk key 780 of the finder switch 700 away from its normal position thereby operatively to associate the telephone instrument at her position with the C. A. X. trunk 510, as previously explained. In the event the subscriber at the called subscriber substation in the exchange D has replaced the

receiver of the telephone instrument therat upon its hook and the subscriber at the calling subscriber substation T3 desires another connection, the operator at the first operator position may release the outgoing end of the dual call connection extending to the exchange D, as previously noted. This is accomplished by operating the dual release key K11 away from its normal position.

When the dual release key K11 is operated away from its normal position, the previously traced circuits for energizing the relay R1240 and the rear split relay R1220 in the relay group 1200A are completed, at the contacts 1421 and 1429, respectively, thereof, thereby to cause the latter relays to operate. Upon operating, the relays R1220 and R1240 complete the previously traced paths for applying ground potential at RC1243 to the wiper 702 of the wiper set of the mechanism 701 in the finder switch 700, thereby to cause ground potential to be applied to the control conductor C636 when the dial-out relay R620 in the C. A. X. trunk circuit 600 operates. Also, upon operating, the relay R1240 completes, at RA1244, the previously traced circuit for energizing the relay R1300 in the relay group 1200A in series with the dial-out relay R620 in the C. A. X. trunk circuit 600, thereby to cause the latter relays to operate. Upon operating, the dial-out relay R620 completes the previously traced path for connecting ground potential to the control conductor C636, as previously noted. This application of ground potential to the control conductor C636 causes ground potential to be applied to the control conductor C515 extending to the dual call control circuit and repeater 500. This application of ground potential to the control conductor C515 causes the dual call control circuit and repeater 500 to operate and release the outgoing end of the connection extending to the exchange D. More particularly, the selector switch 517 in the tandem exchange C and the local switch train in the exchange D are released. The operator at the first operator position then operates the dual release key K11 back to its normal position, thereby to interrupt the previously traced circuits for energizing the rear split relay R1220 and the relay R1240 in the relay group 1200A in order to cause the latter relays to restore. Upon restoring, the rear split relay R1220 recompletes the previously traced connection between the telephone instrument at the first operator position and the finder switch 700. Upon restoring, the relay R1240 interrupts, at RA1244, the previously traced circuit for energizing in series the relay R1300 in the relay group 1200A and the dial-out relay R620 in the C. A. X. trunk circuit 600, thereby to cause the latter relays to restore. Upon restoring, the dial-out relay R620 recompletes the previously traced connection between the telephone instrument at the calling subscriber substation T3 in the tandem exchange C and the telephone instrument at the first operator position. The operator at the first operator position may extend the incoming call from the calling substation T3 to its destination in the previously described manner.

When the operator at the first operator position operates the talk key 780 of the finder switch 700 away from its normal position, thereby to establish an operative connection between the telephone instrument therat and the C. A. X. trunk 510 incident to the illumination of the supervisory lamp L767 and then finds that both the call-

ing and called parties have replaced the receivers of the telephone instruments at their substations upon their respective switchhooks, she completely releases the dual call connection. This is accomplished by operating the release key K8 to its rear position, thereby to cause the finder switch 700 to be released as previously explained. When the finder switch 700 is released, the wiper set thereof is restored to its normal position, thereby to interrupt the previously traced path for applying ground potential to the control conductor C673 of the trunk line 670 in order to interrupt the previously traced circuit for energizing the marking relay R650 in the C. A. X. trunk circuit 600, whereupon the latter relay restores. Upon restoring, the marking relay R650 interrupts, at RA658 and RC658, the previously traced path for connecting battery potential at the resistor 685 to the control conductor C636 and completes, at RA658 and RC659, the previously traced path for connecting ground potential to the control conductor C636. This application of ground potential to the control conductor C636 is conducted by way of the simplex link including the C. A. X. trunk 510 to the control conductor C515 extending to the dual call control circuit and repeater 500. This application of ground potential to the control conductor C515 causes the dual call control circuit and repeater 500 to be released, whereupon the local switch trains in both the tandem exchange C and the distant exchange D are released. At this time the apparatus in the C. A. X. network involved in setting up the dual call is completely released, and the dual call control circuit and repeater 500 in the tandem exchange C and the C. A. X. trunk circuit 600 in the central office A are marked as idle, thereby rendering the C. A. X. trunk 510 available for further use.

40 The operator at the first operator position then returns the release key K8 to its normal position, thereby to cause the remainder of the apparatus at the first operator position to be released. Furthermore, the talk key 780 is returned to its normal position, thereby to cause the finder switch 700 to be completely released, as previously explained.

Extension of a delayed call from the switchboard

50 After a call is answered at one of the operator positions at the switchboard, the operator thereat extends the call to the desired destination in the manner previously explained. In the event the subscriber substation at the destination is busy or all of the trunks extending to an intermediate switching point in the outgoing switch train are busy, the calling party is so advised and subsequently the operator again endeavors to extend the connection to the destination as previously explained. However, in the event the called subscriber substation remains busy or all of the trunk lines extending to an intermediate switching point in the outgoing switch train remain busy, the calling party is advised that the call 65 may not immediately be extended and that when the connection has been extended to the desired destination, he will be recalled. The operator at the first operator position then prepares a ticket for the call, indicating the calling and called substations, and passes this ticket to a point-to-point operator position. The operator at the point-to-point operator position then endeavors to establish a connection from her position to the called subscriber substation and after this connection is established, she establishes a connec-

tion from her position to the calling subscriber substation. This type of call is termed a delayed, point-to-point or tail-to-tail call and will hereinafter be referred to as a delayed call.

Assuming that the operator at the first operator position 1400 wishes to make a delayed call from her position, she first operates the dial rear key K4 away from its normal position. When the dial rear key K4 is operated away from its normal position, the previously mentioned circuit 10 for energizing the relay R1350 in the relay group 1200A is completed, at the contact 1444 thereof, thereby to cause the last-mentioned relay to operate. Upon operating, the relay R1350 completes, at RA1351, the previously traced circuit 15 for energizing the lower winding of the call relay R1340 in series with the lower winding of the call pilot relay R1320, thereby to cause the latter relays to operate. Also, the relay R1350 prepares, at RA1353, a point in the previously 20 traced circuit for applying ground potential to the start conductor C1360 included in the cable 1367 extending to the sender control circuit 300.

Upon operating, the call pilot relay R1320 interrupts, at RA1321, a point in the previously 25 traced circuit for energizing the distributor start relay R1310, thereby to prevent operation of the last-mentioned relay at this time. Upon operating, the relay R1340 prepares, at RA1340, a point in a path, traced hereinafter, for applying 30 ground potential to the release conductor C1461 included in the cable 1286, interrupts, at RA1341 and RC1342, a point in the previously mentioned path for applying ground potential to the guard conductor C1362 included in the cable 1367, 35 thereby to mark the cable 1367 as having a calling condition thereon. Also, the call relay R1340 completes, at RA1341 and RC1343, the previously 40 traced circuit for energizing the rear split relay R1220, thereby to cause the latter relay to operate. Further, the relay R1340 prepares, at RA1344, a point in a holding circuit, traced hereinafter, for energizing the winding of the talk relay R1130 in the relay group 1200A in series 45 with the upper winding of the connect relay in one of the finder switches, completes, at RA1346 and RC1347, the previously mentioned connection between the conductor C1383 included in the cable 1286 and the conductor C1261 included in the cable 1367, 50 interrupts, at RA1346 and RC1348, a point in the previously traced circuit for energizing the supervisory relay R1230, and prepares, at RA1349, a point in the previously 55 traced path for applying ground potential to the start conductor C1360 included in the cable 1367 extending to the sender control circuit 300.

Upon operating, the rear split relay R1220 disconnects the conductors C1275 and C1276 included in the cable 1286 from the line conductors C1180 and C1181 of the trunk circuit at the first 60 operator position and connects the last-mentioned conductors to the line conductors C1365 and C1366. Also, when the dial rear key K4 is operated away from its normal position, there are completed, at the contacts 1445, 1442 and 65 1443 thereof, obvious paths for applying ground potential to the conductors C1458, C1456 and C1455, respectively, included in the cable 1286 for purposes more fully described subsequently.

After operating the dial rear key K4 away from 70 its normal position, as previously explained, the operator at the first operator position selects an idle one of the finder-selector links individually associated with her position, such, for example, as the finder-selector link illustrated, and oper- 75

ates the talk key of the finder switch of the selected finder-selector link away from its normal position. Assuming that the operator at the first operator position 1400 selects the finder-selector link illustrated, when the talk key 780 of the finder switch 700 thereof is operated away from its normal position, the previously traced circuit for energizing the lower winding of the connect relay R750 in the finder switch 700 is completed, thereby to cause the latter relay to operate. Upon operating, the connect relay R750 completes, at RA750, the previously traced circuit including the talk key 780 for energizing the upper winding thereof in series with the winding of the talk relay R1130 in the relay group 1200A. Also, at RA759, the connect relay R750 completes a multiple holding circuit for energizing the upper winding of the connect relay R750 in series with the talk relay R1130, the last-mentioned circuit excluding the talk key 780 and extending from ground at the winding of the talk relay R1130, by way of the winding of R1130, C1183, RA1344, the conductor C1378 in the cable 1286, RA759, RA750 and the upper winding of R750 to battery. As previously noted, ground potential appears upon the conductor C1287 included in the cable 1286. Accordingly, upon operating, the connect relay R750 completes, at RA758, an obvious circuit for energizing the start relay R740 over the grounded conductor C1287, thereby to cause the start relay R740 to operate. Further, the connect relay R750 completes, at RA752' and RC753', an obvious path for connecting the grounded conductor C1455 included in the cable 1286 to the conductor C792 included in the cable 786. This application of ground potential to the conductor C792 included in the cable 786 marks the cable 786 as busy in order to prevent one of the sender control circuits, such, for example, as the sender control circuit 300, from operating and seizing the cable 786 at this time. Also, the connect relay R750 prepares, at RA752 and RA753 and at RA755 and RA756, points in the previously traced path for connecting the wipers 702 and 703 of the wiper set of the mechanism 701 in the finder switch 700 to the conductors C1275 and C1276 included in the cable 1286 and operatively connected to the line conductors C1365 and C1366 of the trunk circuit at the first operator position at this time. The application of ground potential to the conductor C1456 included in the cable 1286 marks in the vertical control contact bank 709 of the mechanism 701 the level wherein the group of trunk lines extending to delayed toll selector switches is terminated in the main contact bank of the mechanism 701, this level being indicated as the first level therein.

Upon operating, the start relay R740 completes, at RA742, the previously traced circuit for energizing the vertical magnet M733 of the mechanism 701, thereby to cause the vertical magnet M733 to operate and drive the wiper set of the mechanism 701 one step in the vertical direction. When the wiper set of the mechanism 701 is driven one step in the vertical direction, the vertical control wiper 708 thereof engages the first contact in the vertical control contact bank 709 having ground potential thereon, thereby to complete a circuit for energizing the lower winding of the switch-over relay R720 in series with the step relay R730, this circuit extending from the grounded conductor C1456 in the cable 1286 by way of the first contact in the vertical control contact bank 709, the associated vertical control wiper 708, the lower winding of R720, RA725 and the winding of R730 to battery. When the above-traced circuit is completed, the step relay R730 operates immediately; however, the switch-over relay R720, being of the slow-to-operate type, operates shortly thereafter. Upon operating, the step relay R730 interrupts, at RA731, a point in the previously traced circuit for energizing the vertical magnet M733. Upon operating, the switch-over relay R720 completes, at RA721, the previously traced holding circuit for energizing the upper winding thereof, the set of switch springs S784 being operated into engagement at this time. Also, upon operating, the switch-over relay R720 interrupts, at RA725, a point in the previously traced circuit for energizing the lower winding thereof in series with the winding of the step relay R730, thereby to cause the latter relay to restore. Also, the 20 switch-over relay R720 interrupts, at RA722 and RC723, a point in the previously traced circuit for energizing the vertical magnet M733 and prepares, at RA722 and RC724, a point in the previously traced circuit for energizing the rotary magnet M734 of the mechanism 701. Upon restoring, the step relay R730 completes, at RA731, the previously traced circuit for energizing the rotary magnet M734, thereby to cause the rotary magnet M734 to operate and drive the wiper set 30 of the mechanism 701 one step in the rotary direction. The rotary magnet M734 and the step relay R730 interact, in the previously described manner, thereby to drive the wiper set of the mechanism 701 step by step in the rotary direction until it engages a contact set in the main contact bank of the mechanism 701 terminating a trunk line extending to an idle delayed toll selector switch. Assuming that the delayed toll selector switch 480 is the first idle delayed toll 40 selector switch in the group, the finder switch 700 continues to operate until the trunk line 475 extending thereto is engaged by the wiper set of the mechanism 701. When the trunk line 475 is seized by the wiper set of the mechanism 701, battery potential appearing upon the control conductor thereof completes the previously traced circuit for energizing the intermediate winding of the electropolarized relay R710, thereby to cause the latter relay to operate exceedingly fast, as previously explained. Upon operating, the electropolarized relay R710 completes, at RA716, the previously traced holding circuit for energizing the lower winding thereof and interrupts, at RA714, a point in the previously traced circuit for energizing the rotary magnet M734, thereby to prevent further operation of the rotary magnet M734. Also, the electropolarized relay R710 completes, at RA718, the previously 50 traced path for short-circuiting the intermediate winding thereof, thereby to cause direct ground potential to be applied to the wiper 707 of the wiper set of the mechanism 701, this application of ground potential to the wiper 707 being effective to cause the delayed toll selector switch 480 to operate, thereby to render the delayed toll selector switch 480 responsive to impulses transmitted thereto. Also, the electropolarized relay R710 completes, at RA711 and RA712, the previously traced path between the wipers 702 and 703 of the wiper set of the mechanism 701 and the conductors C1275 and C1276 included in the cable 1286 and connected to the line conductors C1365 and C1366 of the trunk circuit at the first 60

75

operator position. At this time the wipers 702 and 703 of the wiper set of the mechanism 701 are operatively connected by way of the line conductors of the trunk line 475 to the delayed toll selector switch 480; and the line conductors C1365 and C1366 of the trunk circuit at the first operator position are included in the cable 1367 extending to the sender control circuit 300.

- As previously noted, when the switch-over relay R1270 operates, it completes, at RA1271, the previously traced path for applying battery potential to the release conductor C1461 included in the cable 1286, thereby to complete the previously traced circuit for energizing the answer pilot relay R1260 in the relay group 1200A in order to cause the last-mentioned relay to operate. Upon operating, the answer pilot relay R1260 completes, at RA1264, the previously traced holding circuit for energizing the upper winding of the call relay R1340. Also, the answer pilot relay R1260 completes, at RA1261 and RC1263, the previously traced holding circuit for energizing the start relay R740 in the finder switch 700 and completes, at RA1267, the previously traced alternative circuit for applying ground potential at RA1101 to the start conductor C1360 included in the cable 1367 extending to the sender control circuit 300.

This application of ground potential to the start conductor C1360 included in the cable 1367 extending to the sender control circuit 300 causes the sender control circuit 300 to operate. More particularly, the rotary switch 302 thereof seizes the cable 1367; and the rotary switch 301 thereof seizes a trunk line extending to an idle digit register and control circuit, such, for example, as the trunk line 341 extending to the digit register and control circuit 304. When the sender control circuit 300 seizes the cable 1367, a loop circuit is completed between the sender control circuit 300 and the delayed toll selector switch 480 extending by way of the trunk circuit at the first operator position, the finder switch 700, and the trunk line 475.

The operator at the first operator position then operates the sending key set 303, thereby to register in the digit register and control circuit 304 the directory number of the called subscriber substation, whereupon the digit register and control circuit 304 immediately operates to cause the sender control circuit 300 to operate and transmit the impulses comprising the digits registered over the previously traced loop circuit to the delayed toll selector switch 480. The delayed toll selector switch 480 operates in response to the impulses transmitted thereto in a manner similar to the toll selector switch 800, thereby to extend the connection to the called subscriber substation.

In the event the operator at the first operator position makes an error in recording the digits comprising the directory number of the called subscriber substation in the digit register and control circuit 304, she operates the error key K3 away from its normal position, thereby to complete, at the contact 1445 thereof, the previously traced circuit for energizing the error relay R1270, thereby to cause the error relay R1270 to operate. Upon operating, the error relay R1270 completes, at RA1272, an obvious path for applying ground potential at RA1340 to the release conductor C1461 included in the cable 1286. This application of ground potential to the release conductor C1461 causes the finder

switch 700 to restore to its normal position, in the previously described manner, and also completes an obvious path for short-circuiting the winding of the answer pilot relay R1260, thereby to cause the latter relay to restore. Upon restoring, the answer pilot relay R1260 interrupts, at RA1261 and RC1263, the previously traced holding circuit for energizing the start relay R740. Also, upon operating, the error relay R1270 interrupts, at RA1271, a point in the previously traced path for applying ground potential to the start conductor C1287 included in the cable 1286 and interrupts, at RA1273, a point in the previously traced circuit for applying ground potential to the start conductor C1360 included in the cable 1367 extending to the sender control circuit 300, thereby to cause the sender control circuit 300 to release. After operating the error key K3 away from its normal position, the operator at the first operator position returns the error key K3 to its normal position, thereby to interrupt, at the contact 1445 thereof, the previously mentioned circuit for energizing the error relay R1270. Shortly thereafter the error relay R1270 restores, this relay being of the slow-to-release type. Upon restoring, the error relay R1270 interrupts, at RA1272, the previously traced path for applying ground potential to the release conductor C1461 included in the cable 1286 extending to the finder switch 800 and re-completes, at RA1271, the previously traced original circuit for energizing the start relay R740 in the finder switch 700. The finder switch 700 then operates, in the previously described manner, thereby to select a trunk line extending to an idle one of the delayed toll selector switches such, for example, as the delayed toll selector switch 480, whereupon the answer pilot relay R1260 in the relay group 1200A operates, as previously explained. Upon operating, the answer pilot relay R1260 completes, at RA1261, the previously traced path for applying ground potential to the start conductor C1360 included in the cable 1367 extending to the sender control circuit 300, thereby to cause the sender control circuit 300 to operate in the previously described manner. More specifically, the sender control circuit 300 operates to find the cable 1367 and an idle digit register and control circuit, such, for example, as the digit register and control circuit 304. At this time a loop circuit is again completed between the sender control circuit 300 and the delayed toll selector switch 480, as previously explained. Again the operator at the first operator position 1400 operates the sending key set 303 in order to register in the digit register and control circuit 304 the directory number of the called subscriber substation. The subsequent operation of the delayed toll selector switch 480 to extend the connection to the called subscriber substation is the same as that previously explained.

After the sender control circuit 300 operates to transmit the entire series of digits by way of the trunk circuit at the first operator position, the finder switch 700, the trunk line 475, and the delayed toll selector switch 480 to the local switch train associated therewith, thereby to cause the local switch train to seize the subscriber line extending to the called subscriber substation, the sender control circuit 300 operates to cause ground potential to be applied to the conductor C1364 included in the cable 1367, thus completing the previously mentioned circuit for energizing the cut- 75

- in relay R1330 in the relay group 1200A. The cut-in relay R1330 then operates to complete, at RA1333 and RA1334, the previously traced holding circuit for energizing the winding thereof.
- 5 Also, the cut-in relay R1330 interrupts, at RA1334 and RC1335, the previously traced circuit for energizing the lower winding of the call relay R1340 in series with the lower winding of the call pilot relay R1320 and interrupts, at RA1332, a point in the previously traced circuit for energizing the upper winding of the call relay R1340, thereby to cause the call relay R1340 and the call pilot relay R1320 to restore. The sender control circuit 300 then releases as previously explained.
- 10 Upon restoring, the call relay R1340 interrupts, at RA1341 and RC1343, a point in the previously traced circuit for energizing the rear split relay R1220, thereby to cause the latter relay to restore. Also, the call relay R1340 completes, at RA1341 and RC1342, a point in the previously mentioned path for applying ground potential to the guard conductor C1362 included in the cable 1367 extending to the sender control circuit 300, thereby to remove the marking of a calling condition upon 15 the cable 1367. Further, the call relay R1340 interrupts, at RA1345, a further point in the holding circuit for energizing the upper winding thereof and interrupts, at RA1344, a point in the alternative circuit for energizing the winding of the 20 talk relay R1130 in the relay group 1200A in series with the upper winding of the connect relay R750 in the finder switch 700, the holding circuit for energizing the winding of the talk relay R1130 in series with the upper winding of the connect relay 25 R750 being completed, at this time, only by way of the previously traced circuit including the talk key 780 of the finder switch 700. Further, the call relay R1340 completes, at RA1346 and RC1348, a point in the previously traced path for 30 connecting battery at the winding of the supervisory relay R1230 in the relay group 1200A to the wiper 706 of the wiper set of the mechanism 701 in the finder switch 700 and interrupts, at RA1349, a further point in the previously traced 35 circuit for applying ground potential to the start conductor C1360 included in the cable 1367 extending to the sender control circuit 300.
- Subsequent to the operation of the delayed toll selector switch 480 to seize the trunk circuit 40 50 tending to the local switch train which has seized the called subscriber line at this time, the last-mentioned trunk circuit operates to cause ground potential to be applied by way of the delayed toll selector switch 480 to the control conductors of the trunk line 475 engaged by the wiper 706 of the wiper set of the mechanism 701 of the finder switch 700, thereby to complete the previously traced circuit for energizing the supervisory relay R1230 in the relay group 1200A in order to cause 55 the latter relay to operate. Upon operating, the supervisory relay R1230 completes, at RA1231, the previously traced circuit for illuminating the supervisory lamp L767, thereby to indicate to the operator at the first operator position that the connection has been extended to the called subscriber line. In the event the called subscriber line is busy, the local switch train seizing it operates to cause busy tone current to be transmitted 60 over the previously mentioned connections to the receiver of the telephone instrument at the first operator position 1400; and in the event the called subscriber line is idle, the local switch train operates to cause ringing current to be projected there-over and ring-back tone current to be returned 65 over the previously mentioned connections to the receiver of the telephone instrument at the first operator position, thereby to indicate to the operator thereat that the called subscriber line is being rung. When the subscriber at the called subscriber substation answers the call, the local 5 switch train operates, in the previously described manner, thereby to remove ground potential from the control conductor of the trunk line 475 engaged by the wiper 706 of the wiper set of the mechanism 701 of the finder switch 700, whereupon the previously traced circuit for energizing the supervisory relay R1230 in the relay group 1200A is interrupted, causing the last-mentioned relay to restore. Upon restoring, the supervisory relay R1230 interrupts, at RA1231, the previously 10 traced circuit for illuminating the supervisory lamp L767, thereby to indicate to the operator at the first operator position that the party at the called subscriber substation has answered the call extended thereto. The called party is then advised that a call is to be extended from the switch-board to him, whereupon the operator at the first operator position proceeds to extend a connection by way of the toll selector switch 800 of the finder-selector link illustrated to the original calling 15 party.
- This call is initiated by returning the dial rear key K4 to its normal position. When the dial rear key K4 is returned to its normal position, the previously traced paths for applying ground potential 20 to the conductors C1455, C1456 and C1458 included in the cable 1286 extending to the finder switch 700 are interrupted at the contacts 1443, 1442 and 1445 of the dial rear key K4. Also, at the contact 1444 of the dial rear key K4, the previously traced circuit for energizing the relay R1350 in the relay group 1200A is interrupted, thereby to cause the latter relay to restore. Upon 25 restoring, the relay R1350 interrupts, at RA1351, the previously traced holding circuit for energizing the cut-in relay R1330, thereby to cause the latter relay to restore shortly thereafter, the latter relay being of the slow-to-release type. Upon 30 restoring, the cut-in relay R1330 interrupts, at RA1333 and RA1334, a further point in the holding circuit for energizing the winding thereof and completes, at RA1336, the previously traced original circuit for applying ground potential to the start conductor C1360 included in the cable 1367 35 extending to the sender control circuit 300, a point 50 in the last-mentioned circuit being prepared at RA1352 incident to the restoration of the relay R1350. When ground potential is removed from the conductor C1455 included in the cable 1286, the previously traced path for applying ground 55 potential to the conductor C792 included in the cable 786 is interrupted, thereby to mark the cable 786 as having a calling condition thereon. This application of ground potential to the start conductor C1360 included in the cable 1367 extending to the sender control circuit 300 causes the sender control circuit 300 to operate in the previously described manner. More particularly, the sender control circuit 300 operates to find the cable 786 extending to the finder-selector link 60 illustrated and to find an idle digit register and control circuit, such, for example, as the digit register and control circuit 304.
- The operator at the first operator position 1400 then extends the call over the front end of the 65 finder-selector link illustrated by causing the toll selector switch 800 to operate in the previously described manner. More particularly, the sending key set 303 is operated, thereby to register in the digit register and control circuit 304 the 70 75

directory number of the subscriber line extending to the original calling subscriber substation. The digit register and control circuit 304 then operates to cause the sender control circuit 300 to operate and transmit the impulses comprising the series of digits to the toll selector switch 800. The operations of the toll selector switch 800 and the outgoing switch train in response to the digits transmitted thereto are the same as previously explained.

The supervision and release of the delayed call is the same as that previously explained. Particularly, it is noted that the operator at the first operator position 1400 may release the rear end of the connection including the finder switch 700, the delayed toll selector switch 480, and the local switch train seizing the called subscriber line by operating the release key K8 at her position to its rear position, as previously explained; while the front end of the connection including the toll selector switch 800 and the outgoing switch train may be released by operating the release key K8 to its front position, as previously explained.

Extending local calls in the exchanges

As previously noted, subscribers at the subscriber substations in the central office A may complete calls to other subscriber substations in the central office A unassisted. For example, the subscriber at the subscriber substation T1 in the central office A may extend a call to another subscriber substation in the central office A unassisted. First the subscriber at the substation T1 removes the receiver of the telephone instrument thereat from its hook, thereby to cause the line circuit 961 individually associated with the subscriber line 962 to operate and cause a finder switch, such, for example, as the finder switch 471, to seize the calling subscriber line 962. The subscriber at the calling subscriber substation T1 then actuates the dial mechanism at his substation, thereby to transmit a predetermined series of digits over the subscriber line 962, whereupon the selector switch 472 associated with the finder switch 471 operates to seize the trunk line extending to an idle local connector switch, such, for example, as the local connector switch 470. The subscriber at the substation T1 then actuates the dial mechanism thereat to cause the local connector switch 470 to seize the called subscriber line. Subsequently, the local connector switch 470 operates, in the usual manner, depending upon the idle or busy condition of the called subscriber line. Furthermore, the release of the established connection between the subscriber substations in the central office A is directly under the control of the parties at the substations.

It is noted that some of the subscriber lines in the central office A may be of the party type, rendering it necessary for a party at one of the substations on a party line to initiate a local reverting call. For example, in the event the subscriber line 962 is of the party type, the subscriber at the substation T1 may initiate a local reverting call by removing the receiver of the telephone instrument thereat from its hook, as previously explained, and then dialing a predetermined digit followed by predetermined ring selecting digits after a finder switch, such, for example, as the finder switch 471, has seized the calling subscriber line 962. In response to the first digit dialed, the selector switch 472 associated with the finder switch 471 operates to seize the trunk line extending to the reverting call switch 473, and in response to the ring se-

lecting digits, the reverting call switch 473 operates to cause characteristic ringing current to be projected by way of the selector switch 472 and the finder switch 471 over the subscriber line 962. This characteristic ringing current projected over the subscriber line 962 causes the ringer at the called subscriber substation to operate in a well-known manner. Furthermore, the release of this established connection is under the control of the subscribers in the usual manner.

As previously noted, the subscribers at the subscriber substations in each of the exchanges D and E and in the tandem exchange C may complete calls to other subscriber substations in the respective exchanges without assistance. For example, the subscriber at the substation T3 in tandem exchange C may complete a call to another subscriber substation in the tandem exchange C unassisted. In order to initiate a call of this type, the subscriber at the substation T3 removes the receiver of the telephone instrument from its hook, thereby to cause the line switch 520 associated with the subscriber line 533 extending to the subscriber substation T3 to operate and select an idle selector switch, such, for example, as the selector switch 518. The subscriber at the substation T3 then operates the dial mechanism thereat, thereby to cause the selector switch 518 to operate and seize a trunk line extending to an idle connector switch, such, for example, as the trunk line 530 extending to the connector switch 519. The connector switch is then operated in response to two additional digits transmitted thereto, thereby to seize the called subscriber line. The subsequent operation of the connector switch 519 depends upon the idle or busy condition of the called subscriber line in the usual manner. Furthermore, the release of this connection is under the control of the parties at the calling and called subscriber substations.

As previously noted, the distant exchange B may be of any desired type in which event local calls between the subscriber substations therein may be completed in any well-known manner.

CONCLUSIONS

From the foregoing it is apparent that a telephone system is provided which comprises an automatic switchboard including a number of operator positions and improved automatic switching apparatus controllable from the operator positions for performing the various toll and trunk services in an efficient manner, thereby to insure that toll and trunk calls may be easily set up and supervised at the operator positions at the switchboard.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. In a telephone system, an operator position, a calling switch associated with said operator position, a telephone station, a telephone line extending to said telephone station, an automatic switch having access to said telephone line, a trunk line comprising first and second branches and a trunk circuit, said trunk circuit including a repeater and a normally completed metallic connection between the first and second branches of said trunk line, the first branch of said trunk line being accessible to said calling switch and

the second branch thereof being associated with said automatic switch, operator controlled means at said operator position operative to cause said calling switch to seize the first branch of said trunk line and then to cause said automatic switch to seize said telephone line, thereby to extend a call from said operator position to said telephone station, a signal at said operator position, an operating circuit for said signal, means controlled by the operation of said last-mentioned means for causing said trunk circuit to operate, thereby to interrupt said metallic connection between the first and second branches of said trunk line to complete an operative connection between the first and second branches of said trunk line by way of said repeater and to complete said operating circuit, and means controlled when the call is answered at said telephone station for causing said trunk circuit to operate and interrupt said operating circuit.

2. In a telephone system, an operator position, a calling switch associated with said operator position, a telephone station, a telephone line extending to said telephone station, an automatic switch having access to said telephone line, said automatic switch including ringing apparatus operative to project ringing current over a line seized thereby, a trunk line including first and second branches and an associated trunk circuit, the second branch of said trunk line including a control conductor, the first branch of said trunk line being accessible to said calling switch and the second branch thereof being associated with said automatic switch, operator controlled means at said operator position operative to cause said calling switch to seize the first branch of said trunk line and then to cause said automatic switch to seize said telephone line, thereby to extend a call from said operator position to said telephone station, means controlled by the operation of said last-mentioned means for causing said trunk circuit to operate, means controlled by the last-mentioned operation of said trunk circuit for controlling by way of the control conductor of the second branch of said trunk line the ringing apparatus included in said automatic switch, thereby to prevent operation of the ringing apparatus, additional operator controlled means at said operator position for projecting ringing current by way of said calling switch and the first branch of said trunk line to said trunk circuit, thereby to cause said trunk circuit to operate, and means controlled by the last-mentioned operation of said trunk circuit for controlling by way of the control conductor of the second branch of said trunk line the ringing apparatus included in said automatic switch, thereby to cause operation of the ringing apparatus.

3. In a telephone system, an operator position, a calling switch associated with said operator position, a telephone station, a telephone line extending to said telephone station, an automatic switch having access to said telephone line, said automatic switch including ringing apparatus operative to project ringing current over a line seized thereby, a trunk line comprising first and second branches and a trunk circuit, said trunk circuit including a repeater and a normally completed metallic connection between the first and second branches of said trunk line, the second branch of said trunk line including a control conductor, the first branch of said trunk line being accessible to said calling switch and the second branch thereof being associated with said automatic switch, operator controlled means at

said operator position operative to cause said calling switch to seize the first branch of said trunk line and then to cause said automatic switch to seize said telephone line, thereby to extend a call from said operator position to said telephone station, means controlled by the operation of said last-mentioned means for causing said trunk circuit to operate, means controlled by the last-mentioned operation of said trunk circuit for interrupting said metallic connection between the first and second branches of said trunk line for completing an operative connection between the first and second branches of said trunk line by way of said repeater and for connecting a predetermined potential to the control conductor of the second branch of said trunk line, thereby to prevent operation of the ringing apparatus included in said automatic switch, additional operator controlled means at said operator position for projecting ringing current by way of said calling switch and the first branch of said trunk line to said trunk circuit thereby to cause said trunk circuit to operate, and means controlled by the last-mentioned operation of said trunk circuit for disconnecting the predetermined potential from the controlled conductor of the second branch of said trunk line, thereby to cause operation of the ringing apparatus included in said automatic switch.

4. In a telephone system, an operator position, a calling switch associated with said operator position, a paystation including coin control apparatus, a paystation line extending to said paystation and including two line conductors, an automatic switch having access to said paystation line, a trunk line including first and second branches and an associated trunk circuit, each branch of said trunk line including two line conductors, the first branch of said trunk line being accessible to said calling switch and the second branch thereof being associated with said automatic switch, operator controlled means at said operator position operative to cause said calling switch to seize the first branch of said trunk line and then to cause said automatic switch to seize said paystation line, thereby to extend a call from said operator position to said paystation, additional operator controlled means at said operator position for projecting a current by way of said calling switch and one of the line conductors of the first branch of said trunk line to said trunk circuit, thereby to cause said trunk circuit to operate, and means controlled by the last-mentioned operation of said trunk circuit for connecting both of the line conductors of the second branch of said trunk line to the last-mentioned line conductor of the first branch of said trunk line, thereby to cause current to be projected by way of said automatic switch and both of the line conductors of said paystation line in parallel to said paystation, the coin control apparatus included in said paystation being so connected and arranged that it is operated when current is projected thereto over both of the line conductors of said paystation line in parallel.

5. In a telephone system, an operator position, a calling switch associated with said operator position, a paystation including coin control apparatus, a paystation line extending to said paystation and including two line conductors, an automatic switch having access to said paystation line, a trunk line comprising first and second branches and a trunk circuit, said trunk circuit including a repeater and a normally com-

pleted metallic connection between the first and second branches of said trunk line, each branch of said trunk line including two line conductors, the first branch of said trunk line being accessible to said calling switch and the second branch thereof being associated with said automatic switch, operator controlled means at said operator position operative to cause said calling switch to seize the first branch of said trunk line and then to cause said automatic switch to seize said paystation line, thereby to extend a call from said operator position to said paystation, means controlled by the operation of said last-mentioned means for causing said trunk circuit to operate, means controlled by the last-mentioned operation of said trunk circuit for interrupting said metallic connection between the first and second branches of said trunk line and for completing an operative connection between the first and second branches of said trunk line by way of said repeater, additional operator controlled means at said operator position for projecting a current by way of said calling switch and one of the line conductors of the first branch of said trunk line to said trunk circuit, thereby to cause said trunk circuit to operate, and means controlled by the last-mentioned operation of said trunk circuit for connecting both of the line conductors of the second branch of said trunk line to the last-mentioned line conductor of the first branch of said trunk line, thereby to cause current to be projected by way of said automatic switch and both of the line conductors of said paystation line in parallel to said paystation, the coin control apparatus induced in said paystation being so connected and arranged that it is operated when current is projected thereto over both of the line conductors of said paystation line in parallel.

6. In a telephone system, an operator position, a calling switch associated with said operator position, a telephone station, a telephone line extending to said telephone station, an automatic switch having access to said telephone line, a first trunk line including first and second branches and an associated trunk circuit, the first branch of said first trunk line being accessible to said calling switch and the second branch thereof being associated with said automatic switch, a second trunk line associated with said automatic switch, a selector switch having access to said second trunk line, operator controlled means at said operator position operative to cause said calling switch to seize the first branch of said first trunk line and then to cause said automatic switch to seize said telephone line, thereby to extend a call from said operator position to said telephone station, means controlled by the seizure of the first branch of said first trunk line for causing said trunk circuit to operate, means controlled by the last-mentioned operation of said trunk circuit for marking said second trunk line as busy to said selector switch, means for causing said selector switch to seize said second trunk line, means controlled by the seizure of said second trunk line for causing said trunk circuit to operate, and means controlled by the last-mentioned operation of said trunk circuit for marking the first branch of said first trunk line as busy to said calling switch.

7. In a signaling system, an automatic switch of the type including a wiper set movable in both longitudinal and lateral directions, an associated contact bank provided with a number of longitudinally spaced-apart rows of laterally spaced-

apart contact sets, driving means for moving said wiper set with respect to said contact bank in a longitudinal direction and in a lateral direction, and a control network for governing said driving means; a first group of lines terminated by contact sets disposed in a first row in said contact bank; a second group of lines terminated by contact sets disposed in a second and a third row in said contact bank; and means for controlling said control network; said control network being so connected and arranged that said driving means is selectively governable to cause said wiper set selectively to engage a contact set in said contact bank terminating an idle line in said first group, a contact set in said contact bank terminating an idle line in said second group, and a contact set in said contact bank terminating any particular line in said second group.

8. In a signaling system, an automatic switch of the Strowger type including a wiper set movable in both longitudinal and rotary directions, an associated semi-cylindrical contact bank provided with a number of longitudinally spaced-apart rows of radially spaced-apart contact sets, driving means for moving said wiper set with respect to said contact bank in a longitudinal direction and in a rotary direction, and a control network for governing said driving means; a first group of lines terminated by contact sets disposed in a first row in said contact bank; a second group of lines terminated by contact sets disposed in a second and a third row in said contact bank; and means for controlling said control network, said control network being so connected and arranged that said driving means is selectively governable to cause said wiper set selectively to engage a contact set in said contact bank terminating an idle line in said first group, a contact set in said contact bank terminating an idle line in said second group, and a contact set in said contact bank terminating any particular line in said second group.

9. In a signaling system, first and second groups of lines; an automatic numerical switch having access to said lines and operative to seize one of said lines; a digit responsive control network for governing selectively the operation of said numerical switch; means for transmitting digits to said control network; said control network being so connected and arranged that it is responsive to a given single digit for causing said switch to seize an idle line in said first group, to two given successive digits for causing said switch to seize an idle line in said second group, and to two other successive digits for causing said switch to seize a corresponding particular line in said second group.

10. In a signaling system, an automatic switch of the Strowger type including a wiper set movable in both longitudinal and rotary directions, an associated semi-cylindrical contact bank provided with a number of longitudinally spaced-apart rows of circumferentially spaced-apart contact sets, driving means for moving said wiper set with respect to said contact bank in a longitudinal direction and in a rotary direction, and a digit responsive control network for governing said driving means; a first group of lines terminated by contact sets disposed in a first row in said contact bank; a second group of lines terminated by contact sets disposed in a second and a third row in said contact bank; means for transmitting digits to said control network; said control network being so connected and arranged

- that it is responsive to a given single digit for causing said switch to test the condition of the first line in said first group, to two given successive digits for causing said switch to test the condition of the first line in said second group, and to two other successive digits for causing said switch to test the condition of a corresponding particular line in said second group; means included in said switch and responsive to the test of a busy condition of said first line in either one of said groups for causing said switch to operate automatically and test the condition of the succeeding line in the same group; means included in said switch and responsive to the test of a busy condition of the last line in either one of said groups or of a busy condition of said particular line in said second group for arresting operation of said switch; and means included in said switch and responsive to the test of an idle condition of any one of said lines for causing said switch to seize said one line.
11. In a signaling system, an automatic switch of the type including a wiper set movable in both longitudinal and lateral directions, an associated contact bank provided with a number of longitudinally spaced-apart rows of laterally spaced-apart contact sets, driving means for moving said wiper set with respect to said contact bank in a longitudinal direction and in a lateral direction, and a control network for governing said driving means; a first group of lines terminated by contact sets disposed in a first row in said contact bank; a second group of lines terminated by contact sets disposed in a second and a third row in said contact bank; and means for controlling said control network; said control network being so connected and arranged that it is selectively governable to cause said driving means selectively to move said wiper set successively into engagement with the contact sets disposed in the first row in said contact bank until a contact set is engaged terminating an idle line in said first group, to move said wiper set selectively into engagement with any particular contact set disposed in the second and third rows in said contact bank, and to move said wiper set successively into engagement with the contact sets disposed in the second row in said contact bank until a contact set is engaged terminating an idle line in said second group and then to move said wiper set successively into engagement with the contact sets disposed in the third row in said contact bank until a contact set is engaged terminating an idle line in said second group in the event said wiper set does not engage a contact set in the second row in said contact bank terminating an idle line in said second group, and means for transmitting digits to said control network; said control network being so connected and arranged that it is responsive to a given single digit for causing said switch to seize an idle line in said first group, to two given successive digits for causing said switch to seize an idle line in said second group, and to two other successive digits for causing said switch to seize a corresponding particular line in said second group.
12. In a signaling system, an automatic switch of the type including a wiper set movable in both longitudinal and lateral directions, an associated contact bank provided with a number of longitudinally spaced-apart rows of laterally spaced-apart contact sets, driving means for moving said wiper set with respect to said contact bank in a longitudinal direction and in a lateral direction, and a digit responsive control network for governing said driving means; a first group of lines terminated by contact sets disposed in a first row in said contact bank; a second group of lines terminated by contact sets disposed in a second and a third row in said contact bank; and means for transmitting digits to said control network; said control network being so connected and arranged that it is responsive to a given single digit for causing said switch to move said wiper set successively into engagement with the contact sets disposed in the first row in said contact bank until a contact set is engaged terminating an idle line in said first group, that it is responsive to two given successive digits to cause said driving means to move said wiper set successively into engagement with the contact sets disposed in the second row in said contact bank until a contact set is engaged terminating an idle line in said second group and then to move said wiper set successively into engagement with the contact sets disposed in the third row in said contact bank until a contact set is engaged terminating an idle line in said second group in the event said wiper set does not engage a contact set in the second row in said contact bank terminating an idle line in said second group, and that it is responsive to two other successive digits to cause said driving means to move said wiper set selectively into engagement with any particular contact set disposed in the second and third rows in said contact bank.
13. In a telephone system, an operator position; first and second groups of trunk lines; an automatic switch associated with said operator position; said automatic switch being of the type including a wiper set movable in both longitudinal and lateral directions, an associated contact bank provided with a number of longitudinally spaced-apart rows of laterally spaced-apart contact sets, driving means for moving said wiper set with respect to said contact bank in a longitudinal direction and in a lateral direction, and a control network for governing said driving means; said first group of trunk lines being terminated by contact sets disposed in a first row in said contact bank, said second group of trunk lines being terminated by contact sets disposed in a second and a third row in said contact bank; and operator controlled means at said operator position for controlling said control network, thereby to cause said wiper set selectively to engage a contact set in said contact bank terminating an idle trunk line in said first group, a contact in said contact bank terminating an idle trunk line in said second group, and a contact set in said contact bank terminating any particular trunk line in said second group.
14. In a telephone system, an operator position; first and second groups of trunk lines; an automatic numerical switch associated with said operator position and being operative to seize one of said trunk lines; a digit responsive control network for governing selectively the operation of said numerical switch; and operator controlled means at said operator position for transmitting digits to said control network; said control network being so connected and arranged that it is responsive to a given single digit for causing said switch to seize an idle line in said first group, to two given successive digits for causing said switch to seize an idle line in said second group, and to two other successive digits for causing said switch to seize a corresponding particular line in said second group.
15. In a telephone system, an operator position, a plurality of trunk lines, a finder switch associated with said operator position, said finder switch having access to said trunk lines and being operative to seize any one of said trunk lines having a calling condition thereon, switching apparatus operative to take said trunk lines for use, means for causing operation of said switching apparatus, a trunk distributor oper-

- ative to assign an idle one of said trunk lines to be taken for use, and means controlled when an assigned one of said trunk lines is taken for use for creating a calling condition thereon and for 5 causing said trunk distributor to operate and assign another idle one of said trunk lines to be taken for use.
16. In a telephone system, an operator position, a plurality of main trunk lines and an auxiliary trunk line, a finder switch associated with said operator position, said finder switch having access to said trunk lines and being operative to seize any one of said trunk lines having a calling condition thereon, switching apparatus operating 10 to take said trunk lines for use, means for causing operation of said switching apparatus, a trunk distributor for causing said switching apparatus to take for use in a predetermined order idle ones of said main trunk lines, means controlled when all of said main trunk lines are busy for causing said switching apparatus to take for use said auxiliary trunk line, and means controlled when any one of said trunk lines is taken for use for creating a calling condition thereon.
17. In a telephone system, an operator position, a plurality of trunk lines, a finder switch associated with said operator position, said finder switch having access to said trunk lines and being operative to seize any one of said trunk 15 lines having a calling condition thereon, switching apparatus operative to take said trunk lines for use, means for causing operation of said switching apparatus, a trunk distributor operative to assign an idle one of said trunk lines to be taken for use, means controlled when an assigned one of said trunk lines is taken for use for creating a calling condition thereon and for causing said trunk distributor to operate and assign another idle one of said trunk lines to be taken for use, and means controlled by the operation of said trunk distributor for causing said finder switch to be operated.
18. In a telephone system, an operator position, a plurality of trunk lines, a group of finder switches associated with said operator position, each of said finder switches having access to said trunk lines and being operative to seize any one of said trunk lines having a calling condition thereon, operator controlled means at said operator position for preparing any one of said finder switches to be operated, switching apparatus operative to take said trunk lines for use, means for causing operation of said switching apparatus, a trunk distributor for causing said switching apparatus to take for use in a predetermined order idle ones of said trunk lines, means controlled when any one of said trunk lines is taken for use for creating a calling condition thereon, and means controlled by said trunk distributor for causing a prepared one of said finder switches to be operated.
19. In a telephone system, an operator position, a plurality of trunk lines, a group of finder switches associated with said operator position, each of said finder switches having access to said trunk lines and being operative to seize any one of said trunk lines having a calling condition thereon, operator controlled means at said operator position for preparing any one of said finder switches to be operated, switching apparatus operative to take said trunk lines for use, means for causing operation of said switching apparatus, a trunk distributor for causing said switching apparatus to take for use in a predetermined order idle ones of said trunk lines, means controlled when any one of said trunk lines is taken for use for creating a calling condition thereon, means controlled by said trunk distributor for causing a prepared one of said finder switches in a selected one of said groups to be operated.
- trolled when any one of said trunk lines is taken for use for creating a calling condition thereon, means controlled by said trunk distributor for causing a prepared one of said finder switches to be operated, and additional operator controlled 5 means at said operator position for causing a prepared one of said finder switches to be operated independently of said trunk distributor.
20. In a telephone system, a number of operator positions, a plurality of trunk lines, a finder switch individually associated with each of said operator positions, each of said finder switches having access to said trunk lines and being operative to seize any one of said trunk lines having a calling condition thereon, a position distributor for selecting in a predetermined order said finder switches to be operated, switching apparatus operative to take said trunk lines for use, means for causing operation of said switching apparatus, a trunk distributor for causing said 10 switching apparatus to take for use in a predetermined order idle ones of said trunk lines, means controlled when any one of said trunk lines is taken for use for creating a calling condition thereon, and means controlled by said 15 trunk distributor for causing a selected one of said finder switches to be operated.
21. In a telephone system, a number of operator positions, a plurality of trunk lines, a group of finder switches individually associated with 30 each of said operator positions, each of said finder switches having access to said trunk lines and being operative to seize any one of said trunk lines having a calling condition thereon, operator controlled means at each of said operator 35 positions for preparing any one of the finder switches in the associated group to be operated, a position distributor for selecting in a predetermined order the groups of finder switches in which a finder switch is prepared, switching apparatus operative to take said trunk lines for use, means for causing operation of said switching apparatus, a trunk distributor for causing said switching apparatus to take for use in a predetermined order idle ones of said trunk lines, 40 means controlled when any one of said trunk lines is taken for use for creating a calling condition thereon, and means controlled by said trunk distributor for causing a prepared one of said 45 finder switches in a selected one of said groups to be operated.
22. In a telephone system, a number of operator positions, a plurality of trunk lines, a group of finder switches individually associated with 55 each of said operator positions, each of said finder switches having access to said trunk lines and being operative to seize any one of said trunk lines having a calling condition thereon, operator controlled means at each of said operator positions for preparing any one of the finder switches in the associated group to be operated, a position distributor for selecting in a predetermined order the groups of finder switches in which a 60 finder switch is prepared, switching apparatus operative to take said trunk lines for use, means for causing operation of said switching apparatus, a trunk distributor for causing said switching apparatus to take for use in a predetermined order idle ones of said trunk lines, means controlled when any one of said trunk lines is taken for use for creating a calling condition thereon, and means controlled by said trunk distributor for causing a prepared one of said 65 finder switches in a selected one of said groups to be operated.
- 70

additional operator controlled means at each of said operator positions for causing a prepared one of said finder switches in the associated one of said groups to be operated independently of said 5 trunk distributor.

23. In a signaling system, a plurality of trunk lines, each of said trunk lines including first and second branches and an associated trunk circuit, switching apparatus having access to the first 10 branches of said trunk lines and being operative to search for the first branch of one of said trunk lines marked as idle, a trunk distributor operative to mark as idle the first branch of a selected one of said trunk lines; means for operating said 15 switching apparatus, means responsive to the seizure of the first branch of said selected trunk line for causing the trunk circuit associated therewith to operate, means controlled by the operation of the trunk circuit associated with 20 said selected trunk line for causing the second branch thereof to be marked as having a calling condition thereon and for causing said trunk distributor to operate and mark as idle the first branch of another one of said trunk lines, a finder 25 switch having access to the second branches of said trunk lines and being operative to search for the second branch of one of said trunk lines marked as having a calling condition thereon, and means for causing operation of said finder 30 switch.

24. In a signaling system, a plurality of trunk lines, each of said trunk lines including first and second branches and an associated trunk circuit, each branch of each of said trunk lines including a control conductor, switching apparatus having access to the first branches of said trunk lines and being operative to search for the first 35 branch of one of said trunk lines having a predetermined marking potential on the control conductor thereof, a trunk distributor operative to apply said predetermined marking potential to the control conductor of the first branch of a selected one of said trunk lines, means for operating said switching apparatus, means responsive to the seizure of the first branch of said selected trunk line for causing the trunk circuit associated therewith to operate, means controlled by the operation of the trunk circuit associated with said 40 selected trunk line for causing said predetermined marking potential to be applied to the control conductor of the second branch of said selected trunk line and for causing said trunk distributor to operate and apply said predetermined marking potential to the control conductor of the first branch of another one of said trunk lines, a finder switch having access to the second branches of said trunk lines and being operative to search for the second branch of one of said 45 trunk lines having said predetermined marking potential on the control conductor thereof, and means for causing operation of said finder switch.

25. In a signaling system, a plurality of trunk lines, each of said trunk lines including first and 50 second branches and an associated trunk circuit, switching apparatus having access to the first branches of said trunk lines and being operative to search for the first branch of one of said trunk lines marked as idle, a trunk distributor operative 55 to mark as idle the first branch of a selected one of said trunk lines, means for operating said switching apparatus, means responsive to the seizure of the first branch of said selected trunk line for causing the trunk circuit associated therewith to operate, means controlled by the operation of the trunk circuit associated with said trunk line for marking the first branch thereof as busy for causing 60 a signal voltage to be connected to the first branch thereof and for marking the second branch thereof as having a calling condition thereon, means for causing said finder switch to operate and search for the second branch of said trunk line marked as having a calling condition 65 thereon.

eration of the trunk circuit associated with said selected trunk line for causing a signal voltage to be connected to the first branch thereof for causing the second branch thereof to be marked as having a calling condition thereon and for causing said trunk distributor to operate and mark as idle the first branch of another one of said trunk lines, a finder switch having access to the second branches of said trunk lines and being operative to search for the second branch of one of said trunk lines marked as having a calling condition thereon, means for causing operation of said finder switch, means responsive to the seizure of the second branch of said selected trunk line for causing the trunk circuit associated therewith to operate further, and means controlled by the further operation of the trunk circuit associated with said selected trunk line for causing said signal voltage to be disconnected from the first branch thereof. 20

26. In a telephone system, a subscriber substation, an operator position, a trunk line including first and second branches and an associated trunk circuit, switching apparatus having access to the first branch of said trunk line, means including a subscriber line for operatively associating said subscriber substation and said switching apparatus, a finder switch associated with said operator position and having access to the second branch of said trunk line, means for marking the first branch of said trunk line as idle, means included in said switching apparatus and controlled from said subscriber substation for causing said switching apparatus to operate and search for the first branch of said trunk line marked as idle, means responsive to the seizure of the first branch of said trunk line by said switching apparatus for causing the trunk circuit associated with said trunk line to operate, means responsive to the operation of the trunk circuit associated with said trunk line for marking the first branch thereof as busy and for marking the second branch thereof as having a calling condition thereon, and means for causing said finder switch to operate and search for the second branch of said trunk line marked as having a calling condition thereon. 30

27. In a telephone system, a subscriber substation, an operator position, a trunk line including first and second branches and an associated trunk circuit, switching apparatus having access to the first branch of said trunk line, means including a subscriber line for operatively associating said subscriber substation and said switching apparatus, a finder switch associated with said operator position and having access to the second branch of said trunk line, means for marking the first branch of said trunk line as idle, means included in said switching apparatus and controlled from said subscriber substation for causing said switching apparatus to operate and search for the first branch of said trunk line marked as idle, means responsive to the seizure of the first branch of said trunk line by said switching apparatus for causing the trunk circuit associated with said trunk line to operate, means responsive to the operation of the trunk circuit associated with said trunk line for marking the first branch thereof as busy for causing a signal voltage to be connected to the first branch thereof and for marking the second branch thereof as having a calling condition thereon, means for causing said finder switch to operate and search for the second branch of said trunk line marked as having a calling condition thereon. 40

75

dition thereon, means responsive to the seizure of the second branch of said trunk line by said finder switch for causing the trunk circuit associated with said trunk line to operate further, 5 and means responsive to the further operation of the trunk circuit associated with said trunk line for causing said signal voltage to be disconnected from the first branch thereof.

28. In a telephone system, a subscriber substation, an operator position, a trunk line including first and second branches and an associated trunk circuit, switching apparatus having access to the first branch of said trunk line, means including a subscriber line for operatively associating said subscriber substation and said switching apparatus, a finder switch associated with said operator position and having access to the second branch of said trunk line, means included in said switching apparatus and controlled from said 10 subscriber substation for causing said switching apparatus to seize the first branch of said trunk line, means responsive to the seizure of the first branch of said trunk line by said switching apparatus for causing the trunk circuit associated 15 with said trunk line to operate, means responsive to the operation of the trunk circuit associated with said trunk line for retaining said switching apparatus operated until a release operation is performed at said subscriber substation, means 20 for causing said finder switch to operate and seize the second branch of said trunk line, means responsive to the seizure of the second branch of said trunk line by said finder switch for causing the trunk circuit associated with said trunk line 25 to operate further, means responsive to the further operation of the trunk circuit associated with said trunk line for retaining said switching apparatus operated until a release operation is performed by an operator at said operator position, and means included in the trunk circuit 30 associated with said trunk line and responsive to the performance of a release operation at said subscriber substation prior to the performance of a release operation at said operator position for signaling said operator position.

29. In a signaling system, a plurality of trunks, each of said trunks including first and second branches, automatic switching means having access to the first branches of said trunks, means 35 for causing said switching means to seize in a predetermined order the first branches of idle ones of said trunks, a trunk distributor, means responsive to the seizure of the first branch of a first of said trunks for causing said trunk distributor to operate and mark the second branch of said first trunk as having a calling condition thereon, a number of finder switches, each of said finder switches having access to the second branches of said trunks and being operative to 40 search for the second branch of one of said trunks marked as having a calling condition thereon, means responsive to the seizure of the second branch of said first trunk for causing said trunk distributor to operate and mark the second branch of a second of said trunks as having a calling condition thereon in the event the first branch of said second trunk has been seized, and means for controlling the operation of said finder switches.

70 30. In a signaling system, a plurality of trunks, each of said trunks including first and second branches, automatic switching means having access to the first branches of said trunks, means 45 for causing said switching means to seize in a predetermined order the first branches of idle

ones of said trunks, a trunk distributor, means responsive to the seizure of the first branch of a first of said trunks for causing said trunk distributor to operate and mark the second branch of said first trunk as having a calling condition 5 thereon, a number of finder switches, each of said finder switches having access to the second branches of said trunks and being operative to search for the second branch of one of said trunks marked as having a calling condition thereon, 10 means responsive to the seizure of the second branch of said first trunk for causing said trunk distributor to operate and mark the second branch of a second of said trunks as having a calling condition thereon in the event the first branch 15 of said second trunk has been seized, means for selecting in a predetermined order idle ones of said finder switches to be operated, and means controlled by said trunk distributor for causing a selected one of said finder switches to be 20 operated.

31. In a telephone system, an operator position, a plurality of trunks, each of said trunks including first and second branches, automatic switching means having access to the first branches of said trunks, means for causing said switching means to seize in a predetermined order the first branches of idle ones of said trunks, a trunk distributor, means responsive to the seizure of the first branch of a first of said trunks for causing 25 said trunk distributor to operate and mark the second branch of said first trunk as having a calling condition thereon, a number of finder switches, each of said finder switches having access to the second branches of said trunks and being operative to search for the second branch of one of said trunks marked as having a calling condition thereon, means responsive to the seizure of the second branch of said first trunk for causing said trunk distributor to operate and 30 mark the second branch of a second of said trunks as having a calling condition thereon in the event the first branch of said second trunk has been seized, operator controlled means at 35 said operator position for preparing any one of said finder switches to be operated, and means controlled by said trunk distributor for causing a prepared one of said finder switches to be operated.

32. In a telephone system, an operator position, a plurality of trunks, each of said trunks including first and second branches, automatic switching means having access to the first branches of said trunks, means for causing said switching means to seize in a predetermined order the first branches of idle ones of said trunks, a trunk distributor, means responsive to the seizure of the first branch of a first of said trunks for causing said trunk distributor to operate and mark the second branch of said first trunk as 40 having a calling condition thereon, a number of finder switches, each of said finder switches having access to the second branches of said trunks and being operative to search for the second branch of one of said trunks marked as having a calling condition thereon, means responsive to the seizure of the second branch of said first trunk for causing said trunk distributor to operate and 45 mark the second branch of a second of said trunks as having a calling condition thereon in the event the first branch of said second trunk has been seized, operator controlled means at 50 said operator position for preparing any one of said finder switches to be operated, and means controlled by said trunk distributor for causing a prepared one of said finder switches to be operated.

33. In a telephone system, an operator position, a plurality of trunks, each of said trunks including first and second branches, automatic switching means having access to the first branches of said trunks, means for causing said switching means to seize in a predetermined order the first branches of idle ones of said trunks, a trunk distributor, means responsive to the seizure of the first branch of a first of said trunks for causing said trunk distributor to operate and mark the second branch of said first trunk as 55 having a calling condition thereon, a number of finder switches, each of said finder switches having access to the second branches of said trunks and being operative to search for the second branch of one of said trunks marked as having a calling condition thereon, means responsive to the seizure of the second branch of said first trunk for causing said trunk distributor to operate and 60 mark the second branch of a second of said trunks as having a calling condition thereon in the event the first branch of said second trunk has been seized, operator controlled means at 65 said operator position for preparing any one of said finder switches to be operated, and means controlled by said trunk distributor for causing a prepared one of said finder switches to be operated.

34. In a telephone system, an operator position, a plurality of trunks, each of said trunks including first and second branches, automatic switching means having access to the first branches of said trunks, means for causing said switching means to seize in a predetermined order the first branches of idle ones of said trunks, a trunk distributor, means responsive to the seizure of the first branch of a first of said trunks for causing said trunk distributor to operate and mark the second branch of said first trunk as 70 having a calling condition thereon in the event the first branch of said second trunk has been seized, operator controlled means at said operator position for preparing any one of said finder switches to be operated, and means controlled by said trunk distributor for causing 75

5 a prepared one of said finder switches to be operated, and additional operator controlled means at said operator position for causing a prepared one of said finder switches to be operated independently of said trunk distributor.

10 33. In a telephone system, a number of operator positions, a plurality of trunks, each of said trunks including first and second branches, automatic switching means having access to the first branches of said trunks, means for causing said switching means to seize in a predetermined order the first branches of idle ones of said trunks, a trunk distributor, means responsive to the seizure of the first branch of a first of said 15 trunks for causing said trunk distributor to operate and mark the second branch of said first trunk as having a calling condition thereon, a finder switch individually associated with each of said operator positions, each of said finder switches having access to the second branches of said trunks and being operative to search for the second branch of one of said trunks marked as having a calling condition thereon, means responsive to the seizure of the second branch of said 20 first trunk for causing said trunk distributor to operate and mark the second branch of a second of said trunks as having a calling condition thereon in the event the first branch of said second trunk has been seized, a position distributor for selecting in a predetermined order said finder switches to be operated, and means controlled by said trunk distributor for causing a selected one of said finder switches to be operated.

25 34. In a telephone system, a number of operator positions, a plurality of trunks, each of said trunks including first and second branches, automatic switching means having access to the first branches of said trunks, means for causing said switching means to seize in a predetermined order the first branches of idle ones of said trunks, a trunk distributor, means responsive to the seizure of the first branch of a first of said trunks for causing said trunk distributor to operate and 30 mark the second branch of said first trunk as having a calling condition thereon, a group of finder switches individually associated with each of said operator positions, each of said finder switches having access to the second branches of said trunks and being operative to search for the second branch of one of said trunks marked as having a calling condition thereon, means responsive to the seizure of the second branch of said first trunk for causing said trunk distributor to operate and 35 mark the second branch of a second of said trunks as having a calling condition thereon in the event the first branch of said second trunk has been seized, operator controlled means at each of said operator positions 40 for preparing any one of the finder switches in the associated group to be operated, a position distributor for selecting in a predetermined order the groups of finder switches in which a finder switch is prepared, and means controlled by said 45 trunk distributor for causing a prepared one of said finder switches in a selected one of said groups to be operated.

50 35. In a signaling system, first and second groups of lines, a finder switch having access to said lines, a first distributor normally operative in response to the presence of a calling condition on a line in said first group for causing said finder switch to seize the line in said first group having a calling condition thereon, a second distributor normally operative in response to the 55 presence of a calling condition on a line in said second group for causing said finder switch to seize the line in said second group having a calling condition thereon, and means governed by the operation of one of said distributors for preventing the operation of the other of said distributors.

60 36. In a signaling system, first and second groups of lines, a finder switch having access to said lines, a first distributor operative to cause said finder switch to seize a line in said first group having a calling condition thereon, a first operating circuit for said first distributor, means operative in response to the presence of a calling condition on a line in said first group for normally controlling said first operating circuit, thereby to cause operation of said first distributor, a second distributor operative to cause said 65 finder switch to seize a line in said second group having a calling condition thereon, a second operating circuit for said second distributor, means operative in response to the presence of a calling condition on a line in said second group for normally controlling said second operating circuit, thereby to cause operation of said second distributor, and means governed by the control of one of said operating circuits for preventing the other of said operating circuits from being controlled.

70 37. In a signaling system, first and second groups of lines, a finder switch having access to said lines, a first distributor operative to cause said finder switch to seize a line in said first group having a calling condition thereon, a first start relay operative to cause operation of said first distributor, a first operating circuit for said first start relay, means operative in response to the presence of a calling condition on a line in said first group for normally completing said first operating circuit, a second distributor operative to cause said finder switch to seize a line in said second group having a calling condition thereon, a second start relay operative to cause operation of said second distributor, a second operating circuit for said second start relay, means operative in response to the presence of a calling condition on a line in said second group for normally completing said second operating circuit, and means governed by the operation of one of said start relays for interrupting the operating circuit for the other of said start relays.

75 38. In a signaling system, first and second groups of lines, a finder switch having access to said lines, a first distributor normally operative in response to the presence of a calling condition on a line in said first group for causing said finder switch to seize the line in said first group having a calling condition thereon, a second distributor normally operative in response to the presence of a calling condition on a line in said second group for causing said finder switch to seize the line in said second group having a calling condition thereon, and means governed by the operation of one of said distributors for preventing the operation of the other of said distributors, said first and second distributors being so connected and arranged that said first distributor operates faster in response to the presence of a calling condition on a line in said first group than said second distributor in response to the presence of a calling condition on a line in said second group.

80 39. In a signaling system, first and second groups of lines, a finder switch having access to said lines, a first distributor operative to cause

- said finder switch to seize a line in said first group having a calling condition thereon, a first start relay operative to cause operation of said first distributor, a first operating circuit for said first start relay, said first start relay being relatively fast to operate when said first operating circuit is completed, means operative in response to the presence of a calling condition on a line in said first group for normally completing said first operating circuit, a second distributor operative to cause said finder switch to seize a line in said second group having a calling condition thereon, a second start relay operative to cause operation of said second distributor, a second operating circuit for said second start relay, said second start relay being relatively slow to operate when said second operating circuit is completed, means operative in response to the presence of a calling condition on a line in said second group for normally completing said second operating circuit, and means governed by the operation of one of said start relays for interrupting the operating circuit for the other of said start relays.
40. In a signaling system, first and second groups of lines, a number of finder switches having access to said lines, a first distributor operative to cause idle ones of said finder switches to seize in a predetermined order lines in said first group having calling conditions thereon, said first distributor being so connected and arranged that it is normally operated in response to the presence of a calling condition on a line in said first group and remains operated until all of the lines in said first group having calling conditions thereon are seized by said finder switches, a second distributor operative to cause idle ones of said finder switches to seize in a predetermined order lines in said second group having calling conditions thereon, said second distributor being so connected and arranged that it is normally operated in response to the presence of a calling condition on a line in said second group and remains operated until all of the lines in said second group having calling conditions thereon are seized by said finder switches, and means governed while one of said distributors is operated for preventing operation of the other of said distributors.
41. In a signaling system, first and second groups of lines, a number of finder switches having access to said lines, a first line distributor operative to preselect in a predetermined order idle ones of said finder switches for use, a first line distributor operative to cause selected ones of said finder switches to seize in a predetermined order lines in said first group having calling conditions thereon, said first line distributor being so connected and arranged that it is normally operated in response to the presence of a calling condition on a line in said first group and remains operated until all of the lines in said first group having calling conditions thereon are seized by said finder switches, a second line distributor operative to cause selected ones of said finder switches to seize in a predetermined order lines in said second group having calling conditions thereon, said second line distributor being so connected and arranged that it is normally operated in response to the presence of a calling condition on a line in said second group and remains operated until all of the lines in said second group having calling conditions thereon are seized by said finder switches, and means governed while one of said line distributors is operated for preventing operation of the other of said line distributors.
42. In a signaling system, first and second groups of trunk lines, switching apparatus having access to said first and second groups of trunk lines, means for causing said switching apparatus to take in a predetermined order idle ones of said first trunk lines for use, means for causing said switching apparatus to take in a predetermined order idle ones of said second trunk lines for use, a number of finder switches having access to said trunk lines, each of said finder switches being operative to seize any one of said trunk lines marked as having a calling condition thereon, a first trunk distributor operative to mark the trunk lines in said first group taken for use as having calling conditions thereon and to cause idle ones of said finder switches to be operated, said first trunk distributor being so connected and arranged that it is normally operated when a trunk line in said first group is taken for use by said switching apparatus and remains operated until all of the trunk lines in said first group taken for use by said switching apparatus are seized by said finder switches, a second trunk distributor operative to mark the trunk lines in said second group taken for use as having calling conditions thereon and to cause idle ones of said finder switches to be operated, said second trunk distributor being so connected and arranged that it is normally operated when a trunk line in said second group is taken for use by said switching apparatus and remains operated until all of the trunk lines in said second group taken for use by said switching apparatus are seized by said finder switches, and means governed while one of said trunk distributors is operated for preventing operation of the other of said trunk distributors.
43. In a telephone system, an operator position, first and second groups of trunk lines associated with said operator position, apparatus at said operator position operative to answer a call on any one of said trunk lines, a first distributor normally operative in response to the presence of a call on a line in said first group for rendering the apparatus at said operator position operative to answer the call on the line in said first group, a second distributor normally operative in response to the presence of a call on a line in said second group for rendering the apparatus at said operator position operative to answer the call on the line in said second group, and means governed by the operation of one of said distributors for preventing the operation of the other of said distributors.
44. In a telephone system, a number of operator positions, first and second groups of trunk lines commonly associated with said operator positions, apparatus at each of said operator positions operative to answer a call on any one of said trunk lines, a first distributor operative to render the apparatus at each of said operator positions operative to answer a call on any one of the lines in said first group, said first distributor being so connected and arranged that it is normally operated in response to the presence of a call on any one of the lines in said first group and remains operated until all of the calls on the lines in said first group have been answered, a second distributor operative to render the apparatus at each of said operator positions operative to answer a call on any one of the lines in said second group, said second distributor being so connected and arranged that it is normally

operated in response to the presence of a call on any one of the lines in said second group and remains operated until all of the calls on the lines in said second group have been answered, 5 and means governed while one of said distributors is operated for preventing operation of the other of said distributors.

45. In a telephone system, an operator position, first and second groups of trunk lines, a finder 10 switch associated with said operator position, said finder switch having access to said trunk lines and being operative to seize any one of said trunk lines marked as having a calling condition thereon, means for causing said finder switch to 15 be operated, means operative to take any one of said trunk lines for use, means for causing operation of said last-mentioned means, a first distributor operative to mark as having a calling condition thereon any one of the trunk lines 20 in said first group taken for use, said first distributor being so connected and arranged that it is normally operated when any one of the trunk lines in said first group is taken for use, a second distributor operative to mark as having a calling 25 condition thereon any one of the trunk lines in said second group taken for use, said second distributor being so connected and arranged that it is normally operated when any one of the trunk lines in said second group is taken for use, and 30 means governed by the operation of one of said distributors for preventing the operation of the other of said distributors.

46. In a telephone system, an operator position, first and second groups of trunk lines, a 35 finder switch associated with said operator position, said finder switch having access to said trunk lines and being operative to seize any one of said trunk lines marked as having a calling condition thereon, means operative to take any one of said trunk lines for use, means for causing operation of said last-mentioned means, a first distributor operative to mark as having a calling condition thereon any one of the trunk lines in said first group taken for use and to cause 40 said finder switch to be operated, said first distributor being so connected and arranged that it is normally operated when any one of the trunk lines in said first group is taken for use, a second distributor operative to mark as having a calling condition thereon any one of the trunk lines in said second group taken for use and to cause 45 said finder switch to be operated, said second distributor being so connected and arranged that it is normally operated when any one of the trunk lines in said second group is taken for use, and means governed by the operation of one of said distributors for preventing the operation of the other of said distributors.

47. In a telephone system, an operator position, 50 first and second groups of trunk lines, a group of finder switches associated with said operator position, each of said finder switches being operative to seize any one of said trunk lines marked as having a calling condition thereon, operator 55 controlled means at said operator position for preparing any one of said finder switches to be operated, means operative to take any one of said trunk lines for use, means for causing operation of said last-mentioned means, a first distributor operative to mark as having a calling condition thereon any one of the trunk lines in 60 said first group taken for use and to cause a prepared one of said finder switches to be operated, said first distributor being so connected and arranged that it is normally operated when any one of the trunk lines in said first group is taken for use, a second trunk distributor operative to 65 mark as having a calling condition thereon any one of the trunk lines in said second group taken for use and to cause a prepared one of said finder switches to be operated, said second trunk distributor being so connected and arranged that it is normally op- 70

one of the trunk lines in said first group is taken for use, a second distributor operative to mark as having a calling condition thereon any one of the trunk lines in said second group taken for use and to cause a prepared one of said finder 5 switches to be operated, said second distributor being so connected and arranged that it is normally operated when any one of the trunk lines in said second group is taken for use, and means governed by the operation of one of said 10 distributors for preventing the operation of the other of said distributors.

48. In a telephone system, an operator position, first and second groups of trunk lines, a group of finder switches associated with said operator position, each of said finder switches being operative to seize any one of said trunk lines marked as having a calling condition thereon, operator controlled means at said operator position for preparing any one of said finder 15 switches to be operated, means operative to take any one of said trunk lines for use, means for causing operation of said last-mentioned means, a first distributor operative to mark as having a calling condition thereon any one of the trunk lines in said first group taken for use and to cause a prepared one of said finder switches to be operated, said first distributor being so connected and arranged that it is normally operated when any one of the trunk lines in said first group is taken for use, a second distributor operative to 20 mark as having a calling condition thereon any one of the trunk lines in said second group taken for use and to cause a prepared one of said finder switches to be operated, said second distributor being so connected and arranged that it is normally operated when any one of the trunk lines in said second group is taken for use, and means governed by the operation of one of said distributors for preventing the operation of the other of said distributors.

49. In a telephone system, a number of operator positions, first and second groups of trunk lines, a group of finder switches individually associated with each of said operator positions, each of said finder switches being operative to seize any one of said trunk lines marked as having a calling condition thereon, operator controlled means at each of said operator positions for preparing any one of the finder switches in the associated group to be operated, a position distributor for selecting in a predetermined order the groups of finder switches in which a finder switch is prepared, means operative to take any one of said trunk lines for use, means for causing operation of said last-mentioned means, a first 50 distributor operative to mark as having a calling condition thereon any one of the trunk lines in said first group taken for use and to cause a prepared one of said finder switches in a selected one of said groups to be operated, said first distributor being so connected and arranged that it is normally operated when any one of the trunk lines in said first group is taken for use, a second trunk distributor operative to 55 mark as having a calling condition thereon any one of the trunk lines in said second group taken for use and to cause a prepared one of said finder switches in a selected one of said groups to be operated, said second trunk distributor being so connected and arranged that it is normally op- 60

- erated when any one of the trunk lines in said second group is taken for use, and means governed by the operation of one of said trunk distributors for preventing the operation of the other of said trunk distributors.
5. 50. In a telephone system, an operator position, first and second groups of trunk lines, a group of finder switches associated with said operator position, each of said finder switches being operative to seize any one of said trunk lines marked as having a calling condition thereon, operator controlled means at said operator position for preparing any one of said finder switches to be operated, means for taking any one of said trunk lines for use, means for causing operation of said last-mentioned means, a first distributor operative to mark as having a calling condition thereon any one of the trunk lines in said first group taken for use and to cause a prepared one of said finder switches to be operated, said first distributor being so connected and arranged that it is normally operated when any one of the trunk lines in said first group is taken for use and remains operated until all of the trunk lines in said first group taken for use have been seized by said finder switches, a second distributor operative to mark as having a calling condition thereon any one of the trunk lines in said second group taken for use and to cause a prepared one of said finder switches to be operated, said second distributor being so connected and arranged that it is normally operated when any one of the trunk lines in said second group is taken for use and remains operated until all of the trunk lines in said second group taken for use have been seized by said finder switches, and means governed while one of said distributors is operated for preventing operation of the other of said distributors.
40. 51. In a telephone system, a number of operator positions, first and second groups of trunk lines, a group of finder switches individually associated with each of said operator positions, each of said finder switches being operative to seize any one of said trunk lines marked as having a calling condition thereon, operator controlled means at each of said operator positions for preparing any one of the finder switches in the associated group to be operated, a position distributor for selecting in a predetermined order the groups of finder switches in which a finder switch is prepared, means operative to take any one of said trunk lines for use, means for causing operation of said last-mentioned means, a first trunk distributor operative to mark as having a calling condition thereon any one of the trunk lines in said first group taken for use and to cause a prepared one of said finder switches in a selected one of said groups to be operated, said first distributor being so connected and arranged that it is normally operated when any one of the trunk lines in said first group is taken for use and remains operated until all of the trunk lines in said first group taken for use have been seized by said finder switches, a second trunk distributor operative to mark as having a calling condition thereon any one of the trunk lines in said second group taken for use and to cause a prepared one of said finder switches in a selected one of said groups to be operated, said second trunk distributor being so connected and arranged that it is normally operated when any one of the trunk lines in said second group is taken for use and remains operated until all of the trunk lines in said second group taken for use have been

seized by said finder switches, and means governed while one of said trunk distributors is operated for preventing operation of the other of said trunk distributors.

52. In a telephone system, an exchange provided with a switchboard including an operator position, a plurality of toll lines and a plurality of trunk lines associated with said switchboard, said toll lines being accessible to a distant exchange and said trunk lines being accessible to 10 local subscriber substations, apparatus at said operator position for receiving incoming calls on said lines and for extending and initiating outgoing calls on said lines, means normally operative to route incoming calls on both said toll lines 15 and said trunk lines to said operator position, operator controlled means at said operator position operative to restrict the operation of said last-mentioned means to that of routing incoming calls on said toll lines to said operator position, and means controlled when an outgoing call is initiated at said operator position on one 20 of said lines for preventing the operation of said first-mentioned means to route incoming calls on said lines to said operator position. 25

53. In a telephone system, an exchange provided with a switchboard including a plurality of operator positions, a plurality of toll lines and a plurality of trunk lines associated with said switchboard, said toll lines being accessible to a 30 distant exchange and said trunk lines being accessible to local subscriber substations, apparatus at each of said operator positions for receiving incoming calls on said lines and for extending and initiating outgoing calls on said lines, a 35 distributor operative to select in a predetermined order said operator positions and normally to route incoming calls on both said toll lines and said trunk lines to the selected operator position, operator controlled means at each of said operator positions operative to restrict the operation of said distributor to that of routing incoming calls on said toll lines to the operator position when it is selected, and means controlled when an outgoing call is initiated at any one of said operator positions for preventing said distributor 45 from selecting said one operator position.

54. In a telephone system, first and second exchanges, a trunk extending between said exchanges, automatic switching means in said first exchange having access to said trunk, subscriber lines, subscriber substations associated with said subscriber lines, subscriber controlled means at said substations for causing said switching means to seize said trunk, two automatic switching devices in said first exchange, each of said switching devices being associated with said trunk and having access to said subscriber lines, means controlled in accordance with the seizure of said trunk by said switching means for selecting a 60 first of said switching devices to be operated, an operator position in said second exchange, automatic switching apparatus in said second exchange having access to said trunk, operator controlled means at said operator position for causing said switching apparatus to seize said trunk, means for selecting a second of said switching devices to be operated, and additional operator controlled means at said operator position for controlling the operation of a selected one of said 65 switching devices over said switching apparatus and said trunk.

55. In a telephone system, a trunk, a plurality of lines, automatic switching means having access to said trunk, means controlled over said 70

- lines for causing said switching means to seize said trunk, two automatic switching devices associated with said trunk and having access to said lines, means controlled in accordance with the seizure of said trunk by said switching means for selecting a first of said switching devices to be operated, an operator position, automatic switching apparatus having access to said trunk, means controlled by the seizure of said trunk by said switching means for causing said switching apparatus to seize said trunk, operator controlled means at said operator position operative to cause said switching apparatus to seize said trunk, means controlled in accordance with the seizure of said trunk by said switching apparatus in response to the operation of said operator controlled means for selecting a second of said switching devices to be operated, and additional operator controlled means at said operator position for controlling the operation of a selected one of said switching devices over either one of said switches and said trunk.
56. In a telephone system, a trunk, a plurality of lines, automatic switching means having access to said trunk, means controlled over said lines for causing said switching means to seize said trunk, two automatic switching devices associated with said trunk and having access to said lines, means controlled in accordance with the seizure of said trunk by said switching means for selecting a first of said switching devices to be operated, an operator position, a link including an answer switch and a call switch each having access to said trunk, means for causing said answer switch to seize said trunk when said switching means seizes said trunk, means for causing said call switch to seize said trunk, means controlled in accordance with the seizure of said trunk by said call switch for selecting a second of said switching devices to be operated, and operator controlled means at said operator position for controlling the operation of a selected one of said switching devices over either one of said switches and said trunk.
57. In a telephone system, a trunk, a plurality of lines, automatic switching means having access to said trunk, means controlled over said lines for causing said switching means to seize said trunk, two automatic switching devices associated with said trunk and having access to said lines, means controlled in accordance with the seizure of said trunk by said switching means for selecting a first of said switching devices to be operated, an operator position, a link including an answer switch and a call switch each having access to said trunk, means controlled by the seizure of said trunk by said switching means for causing said answer switch to seize said trunk, operator controlled means at said operator position for causing said call switch to seize said trunk, means controlled in accordance with the seizure of said trunk by said call switch for selecting a second of said switching devices to be operated, and additional operator controlled means at said operator position for controlling the operation of a selected one of said switching devices over either one of said switches and said trunk.
58. In a telephone system, a trunk, a plurality of lines, automatic switching means having access to said trunk, means controlled over said lines for causing said switching means to seize said trunk, two automatic switching devices associated with said trunk and having access to said lines, means controlled when said switching means has seized said trunk for selecting a first of said switching devices to be operated, an operator position, a link including an answer switch and a call switch each having access to said trunk, means controlled by the seizure of said trunk by said switching means for causing said answer switch to seize said trunk, operator controlled means at said operator position for causing said call switch to seize said trunk, means controlled when said call switch has seized said trunk for selecting a second of said switching devices to be operated, and additional operator controlled means at said operator position for controlling the operation of a selected one of said switching devices over either one of said switches and said trunk.
59. In a telephone system, first and second exchanges, a trunk extending between said exchanges, first and second lines, automatic switching means in said first exchange having access to said trunk, means controlled over said first line for causing said switching means to seize said trunk, an automatic switching device in said first exchange, said switching device being associated with said trunk and having access to said second line, an operator position in said second exchange, automatic switching apparatus in said second exchange having access to said trunk, means controlled by the seizure of said trunk by said switching means for causing said switching apparatus to seize said trunk, and operator controlled means at said operator position for controlling the operation of said switching device over said switching apparatus and said trunk, thereby to cause said switching device to seize said second line in order operatively to interconnect said first and second lines.
60. In a telephone system, a trunk, first and second lines, automatic switching means having access to said trunk, an automatic switching device associated with said trunk and having access to said second line, means controlled over said first line for causing said switching means to seize said trunk, an operator position, automatic switching apparatus having access to said trunk, means controlled by the seizure of said trunk by said switching means for causing said switching apparatus to seize said trunk, and operator controlled means at said operator position for controlling the operation of said switching device over said switching apparatus and said trunk, thereby to cause said switching device to seize said second line in order operatively to interconnect said first and second lines.
61. In a telephone system, a trunk, a plurality of lines, automatic switching means associated with said lines and having access to said trunk, an automatic switching device associated with said trunk and having access to said lines, means controlled over a first of said lines for causing said switching means to seize said trunk, thereby to extend a call from said first line to said trunk, an operator position, automatic switching apparatus associated with said operator position and having access to said trunk, means controlled by the seizure of said trunk by said switching means for causing said switching apparatus to seize said trunk, thereby to answer the call on said trunk, operator controlled means at said operator position for controlling the operation of said switching device over said switching apparatus and said trunk, thereby to cause said switching device to seize a second of said lines in order to extend the call from said first line to said second line, and additional operator controlled means at said operator position for controlling the operation of said switching device over said switching apparatus and said trunk, thereby to cause said switching device to seize said second line in order to extend the call from said first line to said second line.

erator position for releasing said switching device without releasing said switching apparatus.

62. In a telephone system, a trunk, a plurality of lines, automatic switching means associated with said lines and having access to said trunk, an automatic switching device associated with said trunk and having access to said lines, means controlled over a first of said lines for causing said switching means to seize said trunk, thereby to extend a call from said first line to said trunk, an operator position, automatic switching apparatus associated with said operator position and having access to said trunk, means controlled by the seizure of said trunk by said switching means for causing said switching apparatus to seize said trunk, thereby to answer the call on said trunk, operator controlled means at said operator position for controlling the operation of said switching device over said switching apparatus and said trunk, thereby to cause said switching device to seize a second of said lines in order to extend the call from said first line to said second line, and means responsive to the performance of a release operation on either said first or said second line for signaling said operator position.

63. In a telephone system, a plurality of trunks, first and second lines, automatic switching means having access to said trunks, automatic switching devices individually associated with said trunks, each of said switching devices having access to said second line, means controlled over said first line for causing said switching means to seize an idle one of said trunks, an operator position, a group of finder switches associated with said operator position, each of said finder switches having access to said trunks and being operative to seize any one of said trunks having a calling condition thereon, operator controlled means for preparing any one of said finder switches to be operated, means controlled when one of said trunks is seized by said switching means for creating a calling condition thereon and for causing a prepared one of said finder switches to be operated, and additional operator controlled means at said operator position for controlling the operation of the switching device individually associated with the trunk seized by an operated one of said finder switches, thereby to cause said last-mentioned switching device to seize said second line in order operatively to interconnect said first and second lines.

64. In a telephone system, a plurality of trunks, first and second lines, automatic switching means having access to said trunks, automatic switching devices individually associated with said trunks, each of said switching devices having access to said second line, means controlled over said first line for causing said switching means to seize an idle one of said trunks, a number of operator positions, a group of finder switches individually associated with each of said operator positions, each of said finder switches having access to said trunks and being operative to seize any one of said trunks having a calling condition thereon, operator controlled means at each of said operator positions for preparing any one of the finder switches in the associated group to be operated, a position distributor for selecting in a predetermined order the groups of finder switches in which a finder switch is prepared, means controlled when one of said trunks is seized by said switching means for creating a calling condition thereon and for causing a prepared one of said

finder switches in a selected one of said groups to be operated, and additional operator controlled means at each of said operator positions for controlling the operation of the switching device individually associated with the trunk seized by an operated one of the finder switches in the associated group, thereby to cause said last-mentioned switching device to seize said second line in order operatively to interconnect said first and second lines. 10

65. In a telephone system, a plurality of trunks, first and second lines, automatic switching means having access to said trunks, automatic switching devices individually associated with said trunks, each of said switching devices having access to said second line, means controlled over said first line for causing said switching means to seize an idle one of said trunks, a number of operator positions, a group of finder switches individually associated with each of said operator positions, each of said finder switches having access to said trunks and being operative to seize any one of said trunks having a calling condition thereon, operator controlled means at each of said operator positions for preparing any one of the finder switches in the associated group to be operated, a position distributor for selecting in a predetermined order the groups of finder switches in which a finder switch is prepared, means controlled when one of said trunks is seized by said switching means for creating a calling condition thereon and for causing a prepared one of said finder switches in a selected one of said groups to be operated, additional operator controlled means at each of said operator positions for controlling the operation of the switching device individually associated with the trunk seized by an operated one of the finder switches in the associated group, thereby to cause said last-mentioned switching device to seize said second line in order operatively to interconnect said first and second lines, and further operator controlled means at each of said operator positions for causing a prepared one of said finder switches in the associated one of said groups to be operated independently. 20

66. In a telephone system, a trunk including two line conductors, a plurality of lines, automatic switching means having access to said trunk, means controlled over any one of said lines for causing said switching means to seize said trunk, two automatic switching devices associated with said trunk and having access to said lines, means controlled in accordance with the seizure of said trunk by said switching means for selecting a first of said switching devices to be operated, an operator position, automatic switching apparatus having access to said trunk, operator controlled means at said operator position for causing said switching apparatus to seize said trunk, means for selecting a second of said switching devices to be operated, and additional operator controlled means at said operator position for controlling the operation of a selected one of said switching devices over a circuit including in series said switching apparatus and the line conductors of said trunk in parallel. 50

67. In a telephone system, a trunk including two line conductors, a plurality of lines, automatic switching means having access to said trunk, means controlled over any one of said lines for causing said switching means to seize said trunk, two automatic switching devices associated with said trunk and having access to said 70 lines.

lines, means controlled in accordance with the seizure of said trunk by said switching means for selecting a first of said switching devices to be operated, an operator position, automatic switching apparatus having access to said trunk, means controlled by the seizure of said trunk by said switching means for causing said switching apparatus to seize said trunk, operator controlled means at said operator position operative to cause said switching apparatus to seize said trunk, means controlled in accordance with the seizure of said trunk by said switching apparatus in response to the operation of said operator controlled means for selecting a second of said switching devices to be operated, additional operator controlled means at said operator position for causing impulses to be transmitted over a circuit including in series said switching apparatus and the line conductors of said trunk in parallel, and means responsive to the impulses transmitted over said trunk for causing a selected one of said switching devices to be operated.

68. In a telephone system, a trunk including two line conductors, first and second lines, automatic switching means having access to said trunk, an automatic switching device associated with said trunk and having access to said second line, means controlled over said first line for causing said switching means to seize said trunk, an operator position, automatic switching apparatus having access to said trunk, means controlled by the seizure of said trunk by said switching means for causing said switching apparatus to seize said trunk, and operator controlled means at said operator position for controlling the operation of said switching device over a circuit including in series said switching apparatus and the line conductors of said trunk in parallel, thereby to cause said switching device to seize said second line in order operatively to interconnect said first and second lines.

69. In a telephone system, a trunk including two line conductors, first and second lines, automatic switching means having access to said trunk, an automatic switching device associated with said trunk and having access to said second line, means controlled over said first line for causing said switching means to seize said trunk, an operator position, automatic switching apparatus having access to said trunk, means controlled by the seizure of said trunk by said switching means for causing said switching apparatus to seize said trunk, operator controlled means at said operator position for causing impulses to be transmitted over a circuit including in series said switching apparatus and the line conductors of said trunk in parallel, and means responsive to the impulses transmitted over said trunk for causing said switching device to seize said second line, thereby operatively to connect said first and second lines.

70. In a telephone system, a trunk including two line conductors, a plurality of lines, automatic switching means associated with said lines and having access to said trunk, an automatic switching device associated with said trunk and having access to said lines, means controlled over a first of said lines for causing said switching means to seize said trunk, thereby to extend a call from said first line to said trunk, an operator position, automatic switching apparatus associated with said operator position and having access to said trunk, means controlled by the seiz-

ure of said trunk by said switching means for causing said switching apparatus to seize said trunk, thereby to answer the call on said trunk, operator controlled means at said operator position for causing control current to flow in a predetermined direction over a path including in series said switching apparatus and the line conductors of said trunk in parallel, means responsive to the flow of control current in said predetermined direction over said path for causing said switching device to seize a second of said lines, thereby to extend the call from said first line to said second line, additional operator controlled means for short-circuiting said path, and means responsive to the short-circuiting of said path for causing said switching device to be released.

71. In a signalling system, an automatic switch of the type including a wiper set movable in both longitudinal and lateral directions, an associated contact bank provided with a number of longitudinally spaced-apart rows of laterally spaced-apart contact sets, driving means for moving said wiper set with respect to said contact bank in a longitudinal direction and in a lateral direction, and a control network for governing said driving means; a first group of lines terminated by contact sets disposed in a first row in said contact bank; a second group of lines terminated by contact sets disposed in a second and a third row in said contact bank; and means for controlling said control network; said control network being so connected and arranged that said driving means is selectively governable to cause said wiper set automatically to hunt for and seize a contact set in said contact bank terminating an idle line in said first group, automatically to hunt for and seize a contact set in said contact bank terminating an idle line in said second group, and positively to seize a contact set in said contact bank terminating any particular line in said second group regardless of the idle or busy condition thereof.

72. In a signaling system, first and second group of lines; an automatic numerical switch having access to said lines and operative to seize one of said lines; a digit responsive control network for governing selectively the operation of said numerical switch; means for transmitting digits to said control network; said control network being so connected and arranged that it is responsive to a given single digit for causing said switch automatically to hunt for and seize an idle line in said first group, to two given successive digits for causing said switch automatically to hunt for and seize an idle line in said second group, and to two other successive digits for causing said switch positively to seize a corresponding particular line in said second group regardless of the idle or busy condition thereof.

73. In a telephone system, a first station, a second station, a repeater, a trunk, means operative to interconnect said first station and said repeater and said trunk, an operator position, automatic switching apparatus operative to interconnect said trunk and said operator position, means controlled by the operation of said last-mentioned means for operating said switching apparatus, means operative to interconnect said repeater and said second station, and operator controlled means at said operator position for controlling over said switching apparatus and said trunk the operation of said last-mentioned means, thereby to establish a three-way communication connec-

tion including said first station and said second station and said operator position.

74. In a telephone system, a first station, a second station, a repeater, a trunk, means operative to interconnect said first station and said repeater and said trunk, an operator position, automatic switching apparatus operative to interconnect said trunk and said operator position, means controlled by the operation of said last-mentioned means for operating said switching apparatus, means operative to interconnect said repeater and said second station, operator controlled means at said operator position for controlling the operation of said last-mentioned means, thereby to establish a three-way communication connection including said first station and said second station and said operator position, and additional operator controlled means at said operator position operative to remove said operator position from said connection while said connection is established between said first station and said second station.

75. In a telephone system, a first exchange, a second exchange, an office, subscriber lines terminating at each of said exchanges and at said office, each of said exchanges and said office including a switch train operative over the subscriber lines terminating thereat to complete connections between the subscriber lines terminating thereat, a repeater, a trunk extending to said office, means operative to interconnect a subscriber line terminating at one of said exchanges and said repeater and said trunk, said office including an operator position and automatic switching apparatus operative to interconnect said trunk and said operator position, means controlled by the operation of said last-mentioned means for operating said switching apparatus, means operative to interconnect said repeater and a subscriber line terminating at the other of said exchanges, and operator controlled means at said operator position for controlling over said switching apparatus and said trunk and said repeater the operation of said last-mentioned means.

45 76. In a telephone system wherein subscriber lines in two automatic exchanges connected by trunk lines complete local automatic connections in the respective exchanges but are restricted from completing inter-exchange calls, an office, a control trunk extending to said office, means operative to seize the control trunk in response to the initiation of an inter-exchange call on a subscriber line in either one of said exchanges, said office including an operator position and automatic switching apparatus operative to establish a connection between said control trunk and said operator position, means controlled by the operation of said last-mentioned means for operating said switching apparatus, thereby to extend the connection to said operator position, and means controlled by the operator at said operator position for revertively extending the connection over said switching apparatus and said control trunk to a subscriber line in either one of said exchanges.

77. In a telephone system wherein subscriber lines in two automatic exchanges connected by trunk lines complete local automatic connections in the respective exchanges but are restricted from completing inter-exchange calls, an office, a control trunk extending to said office, means operative to seize the control trunk in response to the initiation of an inter-exchange call on a subscriber line in one of said exchanges, thereby to

extend the connection to said control trunk, said office including an operator position and automatic switching apparatus operative to establish a connection between said control trunk and said operator position, means controlled by the operation of said last-mentioned means for operating said switching apparatus, thereby to extend the connection to said operator position, means controlled by the operator at said operator position for revertively extending the connection over said switching apparatus and said control trunk to a subscriber line in the other of said exchanges, thereby to establish a three-way communication connection including the subscriber line in said one exchange and the subscriber line in said other exchange and said operator position, and operator controlled means at said operator position operative to remove said operator position from said communication connection while said communication connection is established between the subscriber line in said one exchange and the subscriber line in said other exchange.

78. In a signaling system, a plurality of trunks, automatic switching means having access to said trunks, means for causing said switching means to seize in a predetermined order idle ones of said trunks, a trunk distributor, means responsive to the seizure of a first of said trunks for causing said trunk distributor to operate and mark said first trunk as having a calling condition thereon, a number of finder switches, each of said finder switches having access to said trunks and being operative to search for one of said trunks marked as having a calling condition thereon, means responsive to the seizure of said first trunk by one of said finder switches for causing said trunk distributor to operate and mark a second of said trunks as having a calling condition thereon in the event said second trunk has been seized by said switching means, and means for controlling the operation of said finder switches.

79. In a signaling system, a plurality of trunks, automatic switching means having access to said trunks, means for causing said switching means to seize in a predetermined order idle ones of said trunks, a trunk distributor, means responsive to the seizure of a first of said trunks for causing said trunk distributor to operate and mark said first trunk as having a calling condition thereon, a number of finder switches, each of said finder switches having access to said trunks and being operative to search for one of said trunks marked as having a calling condition thereon, means responsive to the seizure of said first trunk by one of said finder switches for causing said trunk distributor to operate and mark a second of said trunks as having a calling condition thereon in the event said second trunk has been seized by said switching means, means for selecting in a predetermined order idle ones of said finder switches to be operated, and means controlled by said trunk distributor for causing a selected one of said finder switches to be operated.

80. In a telephone system, an operator position, a plurality of trunks, automatic switching means having access to said trunks, means for causing said switching means to seize in a predetermined order idle ones of said trunks, a trunk distributor, means responsive to the seizure of a first of said trunks for causing said trunk distributor to operate and mark said first trunk as having a calling condition thereon, a number of finder switches associated with said operator position, each of said finder switches having access to said

trunks and being operative to search for one of said trunks marked as having a calling condition thereon, means responsive to seizure of said first trunk by one of said finder switches for causing said trunk distributor to operate and mark a second of said trunks as having a calling condition thereon in the event said second trunk has been

seized by said switching means, operator controlled means at said operator position for preparing any one of said finder switches to be operated, and means controlled by said trunk distributor for causing a prepared one of said finder switches to be operated.

THOMAS F. CROCKER.

CERTIFICATE OF CORRECTION.

Patent No. 2,230,052.

January 28, 1941.

THOMAS F. CROCKER.

It is hereby certified that error appears in the printed specification of the above numbered patent requiring correction as follows: Page 65, second column, line 26, claim 3, for the word "controlled" read --control--; and that the said Letters Patent should be read with this correction therein that the same may conform to the record of the case in the Patent Office.

Signed and sealed this 25th day of February, A. D. 1941.

Henry Van Arsdale,
(Seal) Acting Commissioner of Patents.
